UNITED STATES PATENT OFFICE

2,427,049

PRINTING AND CALCULATING MACHINE

Walter T. Gollwitzer, Euclid, Ohio, assignor to
Addressograph-Multigraph Corporation, Wil-
mington, Del., a corporation of Delaware

Application October 27, 1941, Serial No. 416,745

44 Claims. (Cl. 235—61.6)

1

This invention relates to printing machines of the kind particularly adapted for use in the preparation of business instruments and the like of which checks used to pay dividends declared by a corporation are exemplary.

Business instruments of the character prepared in the machine of the present invention usually bear changeable data characterizing or identifying the instruments and which are usually in the form of an address constituting a name, street and number, and city and State. Such instruments also bear variable data, usually expressed numerically, and in the case of a check these data are the amount for which the check is to be payable. Moreover, the instruments bear certain reoccurring data such as the date on which the instrument is issued and, in the case of checks, a signature, and usually such business instruments are numbered, preferably consecutively, and, of course, embody a form such as the name of the issuer and, in the case of checks, the bank whereat it is payable and the like.

The present invention primarily pertains to printing changeable data such as addresses and variable data such as numerical amounts on business instruments such as checks, and also functions to print reoccurring data such as dates, signatures and the like, as well as numbers usually in a consecutive manner, and the primary object of the present invention is to enable this to be effected in a novel manner.

Furthermore, when business instruments are prepared it is usually customary to prepare simultaneously a suitable record which, in the instance where dividend checks are being issued, constitutes a check register and such record is often referred to in the art as a proof sheet, and the present invention also has to do with preparation of a record of this nature simultaneously with the preparation of business instruments.

While a wide variety of devices may be utilized within the purview of the present invention to produce changeable and variable data as aforesaid on business instruments, such as checks, I have shown this effected, in the present instance, from and under control of what are commonly referred to as printing and control devices to which Letters Patent No. 2,132,412, patented October 11, 1938, pertains is exemplary. Resort to the use of a printing and control device of this character enables both the changeable data and the variable data to be produced from a single medium rather than from two mediums as has sometimes been done heretofore, and this is highly advantageous for it avoids the necessity of insur-

2

ing corresponding sequencing in the two series of mediums such as have sometimes been employed heretofore. Furthermore, the present invention is particularly adaptable for producing both changeable and variable data on both a business instrument, such as a check, and a proof sheet, such as a check register, from and under control of printing and control devices which are sequentially passed through the machine to come to rest in stations whereat operations may be performed therefrom or under control thereof to enable production of both changeable and variable data on both a business instrument, such as a check, and a proof sheet, such as a check register, and to enable this to be accomplished in a novel and efficient manner is still another object of the present invention.

Another object of the present invention is to sequentially advance printing and control devices through a machine in a step-by-step manner and to successively bring such devices to rest in positions whereat operations may be performed thereon or under control thereof, and to enable this to be accomplished by disposing mechanisms, adapted for cooperation with the printing and control devices, in spaced apart relation and respectively in association with positions whereat the printing and control devices come to rest, and an object related to the foregoing is to bring the printing and control devices to rest in two spaced apart stations whereat impressions may be made directly therefrom and to enable this to be accomplished in such a way that irrespective of the printing operations being performed at separate and spaced apart stations, an interrelation may be maintained between the data printed at such spaced apart stations.

In instances where, for example, dividend checks are being prepared and in other instances it is often necessary to perform calculating operations to determine data that are to be printed in the course of operation of the machine. For example, in the case of preparation of dividend checks of a corporation, it is advantageous to represent on the respective printing and control devices that are to be passed through the machine the number of shares of stock of the corporation owned by the individual or the like to whom each particular printing and control device pertains and where the number of shares of stock are so represented on a printing and control device, the number of shares of stock is multiplied by the dividend rate to thereby determine the amount for which a particular dividend check is to be payable. Furthermore, when such numerical

amount is ascertained, it is desirable that this amount not only be printed on a business instrument, such as a check, but also upon another record, such as a proof sheet, and preferably such a numerical amount is printed on the business instrument and the like and on the proof sheet in association with the changeable data that is printed thereon from the printing and control device bearing representations of the number of shares of stock and to enable this to be effected in a novel manner is still another object of the present invention; and a related object is to enable changeable data to be printed on a business instrument at one position in a machine and to print variable data on such instrument at such position in the machine and to also print such changeable and variable data on the proof sheet at still another position in the machine, and an object ancillary to the foregoing is to enable the variable data to be printed at each such station and substantially simultaneously, but to enable the changeable data to be printed in different stations but in such relation as to insure accurate relation between the variable and changeable data printed on both the business instruments and the proof sheet; and objects ancillary to the foregoing are to enable changeable and variable data to be simultaneously printed on a record, such as a proof sheet, but in such related positions that the changeable and variable data so simultaneously printed need not be that which is related one to the other; and to so relate operation of the printing means and the means for advancing the record, such as a proof sheet, that variable and changeable data printed simultaneously will be related to other such data printed simultaneously in a way that interrelation on the record between the changeable and variable data will be assured.

A more specific object is to afford two printing stations in a printing machine and to successively bring printing and control devices to rest in such stations so as to enable printing operations to be performed directly therefrom; to provide variable data printing means at each of such printing stations and to enable such means to be so set up and operated that the variable data related to the changeable data at such stations may be printed therefrom; to simultaneously set up the variable data printing means at the two different stations in the machine but at the same time to enable impressions to be made from such means at such times as may be convenient in the course of operation of the machine; to so arrange the variable data printing means disposed at different stations in the machine that while such means may be simultaneously set up, one or the other of such means may be maintained in set-up condition while the other of such means may be restored to a normal or unset-up condition; to enable the variable data printing means to be set up under control of data representations on printing and control devices when such devices are disposed at a position in the machine other than those whereat changeable data is printed from such devices; and to so relate the operations of the setting up the variable data printing means, the advancing of the printing and control devices into the aforesaid printing stations, and the operation of printing means at such stations that variable data printed from the variable data printing means will be printed in predetermined association with changeable data printed from the printing and control device bearing the representation under

control of which the variable data printing means are set up.

In instances where printing and control or like devices are advanced through a plurality of stations in a printing or like machine it is sometimes necessary to advance certain of the printing devices from one station to another at a time when other of the printing devices should remain in stations in which they have been previously advanced, and to enable this to be accomplished is among the important objects of this invention, and objects related to the foregoing are to enable the printing and control device advancing means to be operated each time a printing and control device is to be operated but to enable the printing and control device advancing function of a portion of the printing and control device advancing means to be rendered ineffective when less than all of the printing and control devices that may be advanced by the printing and control device advancing means are to be advanced; to enable the foregoing to be accomplished by members which are operated through a complete cycle of operation each time a printing and control device advancing operation is to be effected, but to enable at least selected of the printing and control device engaging means on such members to be rendered ineffective to advance printing and control devices in the course of operations of such unitary members; and to utilize relatively movable portions for the purpose of advancing printing and control devices through the machine whereby such portions may be either operated to bring about advancing of all of the printing and control devices associated therewith and at the same time to so operate as to enable selected of the printing and control devices to be advanced in an amount greater than that in which others of the devices are advanced.

Further and more specific objects related to the foregoing are to utilize what are commonly called carrier bars for the purpose of advancing the printing and control devices into and from stations whereat such devices are adapted to come to rest in the course of operation of the machine and to equip such carrier bars with printing and control device engaging pawls or the like arranged to be engageable with the printing and control devices to effect advancing thereof upon operation of the carrier bars and to so arrange at least selected of such pawls or the like that they may be rendered ineffective when less than all of the printing and control devices in operative association with the carrier bars are to be advanced in the course of operation of the carrier bars; to impart a uniform movement to carrier bars or the like effective to advance printing and control devices through a like machine but to advance the printing and control devices operatively associated with such carrier bars or the like in varied amounts between the stations whereat the printing and control devices are adapted to come to rest and to enable this to be accomplished even when selected of the printing and control device engaging means on the carrier bars or the like are selectively rendered ineffective; to so arrange carrier bars or the like effective to advance printing and control or like devices through a machine that such bars embody portions which may be operated relative to each other to thereby enable at least selected of such portions to be operated through a distance greater than that through which other portions are operated to thereby enable advancing of selected of the print-

ing and control devices associated with the carrier bars through a distance greater than that through which others are advanced; and to so arrange carrier bars or the like of the aforesaid character that bars may be effective to advance printing and control devices in an amount greater than the travel of such bars or the like to thereby enable at least selected of the printing and control devices associated with the carrier bars or the like to be advanced from one station to another whereat the printing and control devices come to rest and through a distance greater than the amount of normal travel of the carrier bars or the like.

In an instance where proof sheets as, for example, the sheets of a check register are prepared in accordance with the present invention, it is advantageous to include a total at the bottom of each such proof page, and it is also advantageous to produce a total of all of the items printed on all of the pages in a particular group thereof or, in other words, to print what is commonly referred to as a grand total. Furthermore, and particularly where a check register is being prepared, the items are printed thereon in relation to a ledger or other book of account, and it is frequently advantageous to produce a total at the end of a series of items constituting a group as determined by such ledger or other book of account, such a total being commonly known as a ledger total, and among the objects of the present invention are to enable a page total, a ledger total and a grand total to be printed on proof sheets or the like produced in the machine; to enable a page total to be produced automatically as the last item printed on each proof sheet; to enable other operative functions of the machine to be suspended, automatically if desired, so as to enable a ledger total to be taken when the need so to do arises; to enable normal operation of the machine to be suspended when a grand total is to be taken; and to utilize a novel accumulating means for the purpose of accumulating totals as aforesaid and to enable such totals to be printed under control of such accumulators.

In an instance where dividend checks of a corporation are being prepared, and in many other instances where operations are performed under control of data representations such as are borne by the printing and control devices in the present instance, it is not only advantageous to perform calculating operations under control of such data representations but also to enable the data represented by such representations to be printed on sheets or the like in the machine and in the case of dividend checks this enables the number of shares of stock owned by the person or the like to whom the dividend check is to be payable to be printed on the check and, in the present instance, also on the aforesaid check register, and so to do is yet another object of this invention; and objects related to the foregoing are to enable data to be printed, as aforesaid, under control of devices associated with a calculating mechanism included in the machine and, in the present instance, to enable this to be effected through the intermediary of devices included in the multiplying mechanism embodied in the machine; and to enable the foregoing to be effected by devices having structural and operative correspondence with devices included in the calculating mechanism as the multiplying mechanism in the present machine.

In a machine such as that to which the present invention pertains embodying a plurality of

mechanisms adapted to function in operative relation one with the other, it is necessary to insure that accurate timed relation in the operation of such mechanisms be realized and to enable this to be effected in a novel manner is yet another object of the present invention; and objects ancillary to the foregoing are to effect operation of various operative mechanisms in the machine through the intermediary of an electrically controlled clutch or the like; to provide controls for clutches or the like of this character in the form of switches or kindred devices and to so locate such switches or devices in the machine that the aforesaid relation in the operation of the various mechanisms may be assured; and to so arrange the controls for clutches or the like of the aforesaid character or the like that the control thereof may be transferred from one portion of the machine to another when the need so to do arises in the course of the operation of the machine.

In instances where a series of printing and control or like devices are passed through a machine, such as that to which the present invention pertains, there will be instances where certain printing and control devices will be included in the series and yet it will not be desired to perform operations thereon or under control thereof and to this end I so arrange the present machine that selected of the devices may be passed through the machine without having operations performed thereon or under control thereof, and to enable this to be accomplished in a novel manner is a further object of the present invention; and objects ancillary to the foregoing are to insure that proper timed relation among the operative mechanisms in the machine will be assured even when operations are not performed from or under control of selected of the printing control or like devices passed through the machine; and to assure that proper timed relation will be maintained among the various operative mechanisms in the machine even in the event the operation of selective of such mechanisms is suspended for the purpose of taking totals or for other purposes and particularly to insure that the proper relation will be maintained when operation of certain mechanisms in the machine are suspended under circumstances where selected of the printing and control or like devices are being passed through the machine in such a way as not to have operations performed thereon or under control thereof.

In machines of the character to which the present invention pertains it is often necessary to effect special operations as, for example, when a series of printing and control or like devices is first introduced into the machine at a time when no other devices are in the machine it is necessary to send the machine through certain special operations in order to advance printing and control or like devices into positions whereat they will be effective to control certain operative functions of the machine, this being required because it is necessary to have a plurality of printing and control devices respectively disposed at different positions in the machine before the machine will function in the normal automatic manner intended and to enable this to be accomplished is yet a further object of the present invention; and objects ancillary to the foregoing are to so arrange the machine that a control for effecting special operations of the machine may be rendered operative ancillary to placing the machine in operation, and to enable such a special control

to be rendered ineffective when the machine is conditioned in such a way that the operative devices therein will perform their intended functions automatically.

Other and further objects of the present invention will be apparent from the following description and claims and are illustrated in the accompanying drawings which, by way of illustration, show preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

Fig. 63 constitutes a timing chart illustrating the operation of the machine in the skip cycle pertaining to the second of the aforesaid printing devices, and this figure also illustrates the significant features of timing in the normal cycle that follows the second skip cycle;

Fig. 63A is a timing chart illustrating the operation of the machine when but a single skip cycle is to be performed, and this view illustrates the significant portions of the next normal cycle of the machine;

Fig. 64 is a timing chart illustrating the operation of the machine in a normal page total cycle thereof, this view including portions of the preceding normal cycle wherein the automatic controls for the normal page total cycle are set in operation;

Fig. 65 is a timing chart illustrating a portion of a normal cycle wherein the controls for a ledger total cycle are set in operation; and,

Fig. 66 is a timing chart illustrating the operation of the machine in a ledger total cycle and in the special page total cycle that precedes such a ledger total cycle.

The novel machine embodying my invention, generally illustrated in Figs. 1 and 2, is constituted and arranged to produce dividend checks as S, Fig. 3, and proof sheets as PS1, PS2 and PS3, Figs. 5, 6 and 7. The dividend check includes a main body Sm and a stub Sb joined together along a weakened portion SL to facilitate separation thereof.

As can best be ascertained by reference to Fig. 3, the check bears constantly reoccurring data C including, for example, the name and location of the company issuing the check, the words "Number" and "Shares" and kindred data as well as the border appearing on the check. The check also bears changing data A constituting an identification and characterizing the check and in the present instance this is an address comprising a name, street and number, and city and State. Variable data V1 are also printed on the check and constitute, in this instance, the amount for which the check is to be payable, as well as variable data V2 which, in this instance, is the number of shares of stock owned by the person to whom the check is payable, both these data, in some instances hereinafter, being referred to as the variable data V. The check also bears other data such as the date E on which it was issued, a number N and a signature SN.

The various data which appear on the check are, in the present instance, either printed on the check prior to the time it is introduced into the machine or such data are printed on the check in the course of passage thereof through the machine, as will be explained more fully hereinafter. It is to be understood, however, that while in the present instance each check as S is cut to size and, for example, has the constantly reoccurring data C printed thereon prior to the time each such blank check, along with other similar blank checks, is introduced into the machine, each such blank check might be cut from a web and, for example, the reoccurring data C, as well as other data, might be printed thereon prior to the time the blank check is severed from the web and deposited on conveying means operative to carry the check through the machine to have other data printed thereon, and this could be done, for example, by resorting to an arrangement such as that described and claimed in Letters Patent No. 2,041,183, patented May 19, 1936.

In the present instance the address or changing data A are printed on the check directly from type characters as T, Fig. 4, on a printing and control device as D and the variable data V are printed under control of such a printing and control or like device. It is preferred to employ a printing and control device as D in the present machine for so to do eliminates the necessity of checking printing devices or the like bearing, for example, type characters as T against separate record cards or the like, under control of which the variable data as V could be printed, for the printing and control devices as D including both type characters as T and means under control of which variable data as V may be printed insure that, in the course of operation of the present machine, the changing data as A printed from type characters T and the variable data as V will

be printed on a particular check as S so as to thereby insure that related data A and V appear on a single check, it being understood that the type characters T and the means under control of which the variable data V are printed and which are related one to the other are embodied in a single printing and control device as D.

It is to be understood, however, that while reference is made herein to printing and control devices and that while such a device is illustrated and particularly described herein, there are many devices which are applicable for use in the present machine for the present machine might be arranged to utilize devices which constitute either only a printing means or only a control means and that therefore, in so far as certain mechanisms in the present machine are concerned, for example, the means operative to advance the printing and control devices D through the machine, the term printing and control device is used herein in a generic rather than in a limiting and strictly definitive sense.

The printing and control devices D used in the present machine are stored in a drawer as J, Fig. 1, or the like when not in use and when these devices are to be passed through the machine, they are introduced into the magazine H, Fig. 1, provided at the rear of the machine. Novel means are provided for withdrawing the printing devices D one by one from the magazine H and these means are operative to advance these devices through the machine in a step-by-step manner so that the printing and control device successively come to rest in positions or stations whereat printing, sensing or other operations may be performed thereon or under control thereof, and after the devices have been advanced through such stations in the machine they pass through a discharge chute adapted to receive these devices.

The present machine is equipped with an arrangement whereby the printing and control devices, after passage thereof into the aforesaid discharge chute, are returned to the drawer J or the like from which they were removed when they were introduced into the magazine H. To this end suitable means are provided in the machine for the reception of two drawers as J, as shown in Fig. 1. Arrangements, for example, to which resort may be had for so supporting drawers as J in the machine, and for insuring the return of the printing and control devices to the drawer or the like from which they were removed when introduced into the magazine H, are those which are disclosed in my copending application Serial No. 403,272, filed July 21, 1941, now issued as Patent No. 2,390,583, patented December 11, 1945.

PRINTING AND CONTROL DEVICE

A typical printing and control device which may be utilized in the present machine is illustrated in Fig. 4 and is of the character constituting the subject matter of Letters Patent No. 2,132,412, patented October 11, 1938. It is to be understood, however, that this device is typical of other devices which may be utilized in the machine for while the aforesaid printing and control device embodies a metal plate on which the aforesaid type characters T are embossed and includes a card which overlies a portion of the 70 carrier or frame of the printing and control device, so that data representations may be afforded by perforations in such card and frame, resort could be had to a cardboard or other carrier in which data representing perforations, embossures 75 reference to Fig. 2, the platens MP and PP are

or the like might be formed, and such a frame might embody, for example, a stencil paper in which type characters from which impressions might be made might be cut.

5 The typical present printing and control device illustrated in Fig. 4 includes a frame 75 having, in this instance, a metallic plate 76 removably retained thereon by fixed retaining devices 77, a bead 78 at the lower end edge of the frame 75 and yieldable or depressible retaining tongues 79. When one or the other of the tongues 79 is depressed, the plate 76 may be slid endwise from the retaining devices 77 and the bead 78 to thereby enable one such plate as 76 to be replaced by another such plate when the need so to do arises as, for example, upon a change in the post office address of the person or the like whose name may be printed from type characters as T included on the plate 76. In the present instance the type characters T are embossed on the metallic plate 76 to appear in relief on one face thereof and in intaglio on the opposite face, impressions being made from the relief faces of the type characters T when the printing and control device D is fed into printing relation with the platens included in the machine that are described hereinafter.

10 The printing and control device D shown in Fig. 4 also bears a card 80 on which an impression is made from at least selected of the type characters T so that the data which may be printed from the type characters T may be readily ascertained whereby handling of the device D for filing and like purposes is facilitated. The card 80 is 15 removably retained on the frame 75 above the plate 76 by suitable retaining devices 81 and the bead 82 along the top edge of the frame.

20 In the present instance the card 80 is of a length substantially equal to the length of the printing plate 76 and therefore extends over an area of the frame whereat coded data representing perforations may be formed, and to this end the printing and control device D, as viewed in Fig. 4, has the impression 83, made from at least selected of the type characters T on this card 25 confined to the left-hand portion of this card so that the right-hand end of this card affords an area whereat the coded data representing perforations 85 may be formed, and for the purpose of this description the aforesaid card 80 will herein-after be referred to as a control card.

30 While the coded perforations 85, or other data representations, as embossures or the like, may be produced on the frame 75 or the card 80 and this frame in accordance with any desired code 35 so as to be representative of numerical or other data, I prefer to produce these perforations in accordance with the code illustrated in Fig. 4A for so to do enables me to utilize a multiplying mechanism M, such as is described hereinafter and in full detail in my copending applications Serial Nos. 313,146 and 313,147, both filed on January 9, 1940, and now issued as Patent Nos. 2,296,276 and 2,296,278 respectively both patented 40 September 22, 1942.

SHEET FEEDING AND FORM PRINTING

45 In the present instance impressions are made from type characters as T on the printing and control device as D onto the check as S by a main platen MP, Figs. 2 and 8, and similar impressions are made onto the web W by what will be referred to hereinafter as the proof printing platen PP, Figs. 2 and 8. As can best be ascertained by 50 reference to Fig. 2, the platens MP and PP are

aligned one with the other along the guideway G, Figs. 11, 14, 15, 18 and 19, through which the printing and control devices are advanced from the magazine H to the discharge chute 231, Figs. 8 and 18, referred to hereinabove and described hereinafter.

As explained hereinabove, the checks or sheets as S, in the present instance, are cut to size and have certain data printed thereon prior to the time they are introduced into the machine to be fed therethrough and in the illustrated machine the sheets are mounted on the sheet supporting platform 86, Fig. 1, of the sheet feeder SR which operates to withdraw the most inwardly disposed of such sheets from the stack thereof disposed on the platform 86 and thereafter to pass such sheet into the machine. While resort may be had to various types of sheet withdrawing means, that disclosed in my copending application Serial No. 416,636, filed October 27, 1941, now issued as Patent No. 2,342,190, patented February 22, 1944, is typical of the means to which resort may be had for the purpose of withdrawing the sheets or checks one at a time from the supply thereof introduced into the machine as by being disposed on the platform 86.

Moreover, resort may be had to an arrangement such as that shown and described in my copending application Serial No. 239,562, filed November 8, 1938, now issued as Patent No. 2,288,350, patented June 30, 1942, and in such circumstances the sheet receiver SR is supplanted by a web supporting, feeding and severing means such as described in my last referred to copending application which functions to sever sheets from the web and to deposit the sheets on the sheet conveying means, generally indicated by 87, Fig. 2, which may be, for example, of the character shown and described in Letters Patent No. 2,211,772, patented August 20, 1940, the sheet advancing means 87 being described hereinafter with reference to the operation of the machine.

The sheet conveying means 87 is not only operative to advance the sheets or checks as S through the machine but also functions to bring the sheets to rest in operative association with the platen MP and a printing and control device disposed in printing relation therewith to thereby have impressions made on the sheets as S at selected positions thereon, the variable data as V also being printed on the checks as S when they are disposed in operative relation with the platen MP as aforesaid.

After, for example, changeable data as A and variable data as V have been printed on the checks as S during the time they are disposed in operative association with the platen MP, the sheet conveying means 87 functions to advance the sheets to the printing couple PC, Figs. 1 and 2, which may be, for example, of the character disclosed in Letters Patent No. 1,955,814, patented April 24, 1934, or in Letters Patent No. 2,165,535, patented July 11, 1939. However, in the illustrated machine, I employ a well-known printing unit embodying a printing roller and a platen roller and so arranged that either separate type or an electroplate may be mounted on the printing roller, and reference may be had to, for example, Letters Patent Nos. 816,311, 970,441, 990,207, 1,031,311, 1,094,065, 1,148,940 and 1,647,560 for a full disclosure of a printing couple or unit suitable for the purposes of the present invention.

Upon passage of the sheets from the printing couple PC, the sheets are discharged to a suitable

sheet collector as SC to be stacked one upon the other in the usual manner shown, for example, in Fig. 1.

When the printing and control devices advance into operative association with the platen PP, impressions are made therefrom, as stated above, on the web W which is advanced into printing relation with the printing platen PP and a printing and control device disposed in printing relation therewith to have impressions made therefrom, for example, of changeable data A and variable data V, and after passage of those portions of the web W which receive such impressions, the web W is divided into pages. Hence, the means operative to feed the web W to and from operative relation with the platen PP constitute what is known as a pager and proofer mechanism. In the present instance I have shown a pager and proofer mechanism PM, Figs. 1 and 2, generally of the character shown and described in my copending application Serial No. 320,778, filed February 26, 1940, now issued as Patent No. 2,355,796, patented August 15, 1944, but it is to be understood that resort might be had to other equivalent arrangements for feeding the web into printing relationship with the platen PP and for thereafter dividing the web into what are called proof pages.

MACHINE DRIVE

The printing and control devices D that are introduced into the magazine H to be withdrawn therefrom one at a time are fed into printing relation with the platens MP and PP, and these printing and control devices, in the course of advancing movement thereof, also come to rest in other position in the machine whereat operations are performed under control thereof. It is therefore essential that the printing and control devices be advanced through the machine in a definite timed relation and furthermore it is necessary that the functioning of the various mechanisms included in the machine also be brought about in a definite timed relation. In order to insure that this may be brought about I have so arranged the various operative mechanisms in the machine that they may be driven from a main drive shaft which constantly operates when the machine is to be in operation, and I have provided means driven by this main drive shaft which are operative to insure functioning of the various operative mechanisms in the machine in definite timed relation with each other.

Therefore, a main drive shaft 90, Fig. 9, is journaled in suitable bearings provided in the main frame F of the machine. A pulley 91 is fast on the main drive shaft 90 and an endless belt 92 is passed about this pulley and about a pulley 93 fast on the shaft 94 of the motor 95 carried by the bracket 96 secured to the main frame F.

A pinion 97, Figs. 9, 41 and 42, is fast on the drive shaft 90 and meshes with a gear 98 fast to the shaft 99 suitably journaled in bearings in the brackets 100 and 101 carried by the frame F. A bevel gear 102 fast on the shaft 99 is meshed with a bevel gear 103 at the lower end of the vertical shaft 104 journaled in a bearing 105 carried by the bracket 101 and in a bearing 106, Figs. 41 and 42, provided in the frame F. In a manner that will be described in detail hereinafter, the shaft 104 is effective to drive the primary timing means of the machine and other operative mechanisms thereof as, for example,

the operative parts of the sheet conveying means 81.

PRINTING AND CONTROL DEVICE ADVANCING MEANS

A pulley 107, Fig. 9, is fast on the drive shaft 90 on an end thereof projected slightly beyond an adjacent part of the frame F and an endless belt 108 is passed about this pulley and a pulley 109 fast on the shaft 110, Figs. 10 and 11, journaled in suitable bearings provided on a bracket 111 secured at one end to a cross brace 112 of the frame F and which, at the other end thereof, is supported by a bracket 113 secured to the side plate 123 of the printing and control device guideway G described presently. The bracket 111 includes two upstanding and spaced apart arms 114 and 115, Figs. 9 and 11, in which a shaft 117 is journaled. A gear 118 is rotatably mounted on the shaft 117 and meshes with a pinion 119 that is fast on the shaft 110. Thus whenever the main drive shaft 90 is set in operation, the belt 108 transmits this rotative movement to the pulley 109 to thereby set the shaft 110, pinion 119 and gear 118 in operation and at suitable times in the course of operation of the machine a clutch 120 on the shaft 117 connects this shaft to the gear 118 to thereby reciprocate the carrier bars 121 and 122, Fig. 11, of the printing and control device advancing means in operation.

The carrier bar 121 is mounted to be disposed against the inner face of the side plate 123 of the printing and control device guideway G while the carrier bar 122 is disposed against the inner face of the other side plate 124 of the printing and control device guideway. As best shown in Fig. 18, a bar 125 is secured to the inner face of the side plate 124 near the front end thereof and the lower edge of the carrier bar 122 is rested on this bar. Another bar 126, Fig. 20, is mounted on the inner face of the side plate 124 and affords a support for the rear end of the carrier bar 122. These two bars together with other means, explained presently, support the carrier bar 122 against downward displacement and a bar 127, Fig. 11, is secured to the inner face of the side plate 123 opposite the bar 125 and another bar (not shown) similar to the bar 126 is also secured to the inner face of the side plate 123, and these two bars hold the carrier bar 121 against downward displacement.

The carrier bars 121 and 122 are adapted to reciprocate over the inwardly disposed faces of the side plates 123 and 124, and in order to insure interconnection of these carrier bars and to assist in insuring against displacement thereof from the inwardly disposed faces of the side plates 123 and 124, a bracket 128, Figs. 10, 11 and 14, is extended between the carrier or feed bars 121 and 122 and includes upstanding plates 129 and 130, Figs. 11 and 18, which are respectively secured to the carrier bars 121 and 122, this arrangement being effective to insure against displacement of the forward ends of the carrier bars and, as stated, serves to interconnect these bars to insure movement thereof in unison.

As will be explained presently, the carrier bars 121 and 122 are effective to advance the printing and control devices D through the guideway G in a step-by-step manner and these bars are effective to bring the printing and control devices D to rest, in the course of such step-by-step advancing thereof, on the anvils 131 and 132, Figs. 14 and 18, that are operatively and respectively associated with the platens MP and PP. The 75

anvil 131 extends between and is firmly secured to the side plates 123 and 124 substantially midway in the extent of these side plates, while the anvil 132 extends between and is firmly secured to these side plates near the forward ends thereof.

The anvil 131 is slotted as at 133, Fig. 14, to receive and guide the carrier bar 122 and the anvil 132 is similarly slotted at 134. Furthermore, the anvil 131 is slotted at 135 to receive the carrier bar 121 and the anvil 132 is similarly slotted as indicated at 136, these arrangements aiding in retaining the carrier bars in position on the inner faces of the side plates 123 and 124.

It is of course important that the side plates 123 and 124 and the anvils 131 and 132 carried thereby be rigidly supported in position, and this is accomplished in the present instance by rigidly supporting the side plates from the frame F of the machine. To this end a pair of sleeves 137 and 138, Fig. 8, are extended between and secured to the side members of the frame F in spaced apart relation, these sleeves being sufficiently rigid to withstand the stresses that will be impressed thereon in the course of operation of the machine. An upright support 139, Figs. 8 and 9, projects upwardly from the cross sleeve 137 substantially midway between the side members of the frame, and a similar upright support

140, Figs. 8 and 11, projects upwardly from the sleeve 138 in alignment with the support 139. A bracket 141, Figs. 8, 11 and 17, is secured to the upper end of the upright 140 and includes arms 142 and 143 which have rabbets as 144 and 145, Fig. 11, respectively provided in the outwardly disposed faces thereof, and the side plates 123 and 124 are respectively disposed in the rabbets 144 and 145 and are secured to the arms of the brackets 142 and 143 by screws as 146.

Fig. 17. A similar bracket 147, Figs. 9 and 19, is provided at the upper end of the support 139 and the side plates 123 and 124 are secured thereto in the same manner as that in which these side plates are secured to the bracket 141. Thus the sleeves 137 and 138, the uprights 139 and 140 and the brackets 141 and 147 afford a rigid support for the side plates 123 and 124 from the frame F of the machine.

As best shown in Fig. 18, the upper part of the bracket 141 is spaced well below the feed bars as 122 but the bracket 147, Fig. 20, is sized to project upwardly into the path of the feed bars 121 and 122 and, as best shown in Fig. 15, a slot 148 is formed in the bracket 147 similar to the manner in which the slot 133 is formed in the anvil 131, and the disposition of the carrier bar 122 in this slot serves to insure that the rear end portion of this carrier or feed bar will remain in engagement with the inner face of the side plate 124. A similar slot 149 in the bracket 147 similarly cooperates with the carrier bar 121. It will therefore be seen that the bracket 128 serves to interconnect the carrier bars 121 and 122, and this bracket together with the slots 134 and 136 in the anvil 132, the slots or recesses 133 and 135 in the anvil 131 and the slots or recesses 148 and 149 in the bracket 147 serve to maintain the carrier bars tightly against the inner faces of the side plates 123 and 124.

Furthermore, the bottoms of the aforesaid slots are aligned with the upper faces of the bars as 125 and 126, Figs. 18 and 19, and also serve to insure against downward displacement of the carrier bars 121 and 122 in the course of reciprocation thereof.

The printing and control devices D are, in the present machine, disposed in five different stations in the at rest intervals in the step-by-step advancing movement imparted thereto by the carrier bars 121 and 122. Referring for example to Fig. 8, when the printing and control devices are introduced into the magazine H, the lowermost printing and control device in the stack thereof introduced into the magazine H is disposed at station I in the guideway G for the printing and control devices. When the lowermost printing and control device is first advanced from station I at the bottom of the magazine H, it comes to rest at the end of the forward movement that is imparted to the carrier bars 121 and 122, in a manner to be described presently, in station II which will be referred to hereinafter as the sensing station. Thereafter, this printing and control device is advanced from station II to station III where it is disposed on the anvil 131 in printing relation with the main platen MP. This printing and control device next advances to intermediate station IV which, as can be ascertained best by reference to Fig. 8, is located intermediate station III associated with the main platen MP and station V at the anvil 132 to thereby be disposed in printing relation with the proofer platen PP.

By reference to Fig. 8 it will be seen that the distance between the aforesaid stations in which the printing and control devices come to rest in the course of the step-by-step advancing thereof are not uniform for the distance from station II to station III is greater than the distance between any of the other stations whereat the printing and control devices are to come to rest. It will be appreciated that there will be instances where it will be advantageous to have the greatest spacing between stations I and II or, for example, between stations III and IV, and furthermore there will be instances, as in the case of the modified form of my invention described herein-after, where it will be desirable to advance a printing and control device from, for example, station III to station V in the course of a single reciprocation of the carrier bars.

However, in determining the amount of reciprocation that is to be imparted to carrier bars as 121 and 122, it is first ascertained the greatest distance it is desired to move the printing and control devices from one station to another by unitary carrier bars as 121 and 122. In the present instance where this greatest distance is from station II to station III, an arrangement is afforded whereby the amount of reciprocation that will be imparted to the carrier bars 121 and 122 will be sufficient to insure, upon movement of the carrier bars in the forward direction in the reciprocation thereof, that a printing device will be advanced from station II to station III. It is necessary to impart to the carrier bars in such an instance a reciprocatory stroke slightly greater than the actual distance between the most remote stations as, for example, station II and station III in the present instance, in order to afford what might well be called operative clearance for the printing and control advancing pawls which are provided on the carrier bars 121 and 122 in a manner explained presently. However, once the amount of movement that must be imparted to the carrier bars is ascertained, the means for imparting reciprocatory movement to the printing and control devices are arranged to insure that such movement will be imparted thereto.

In the present instance reciprocatory movement is imparted to the carrier bars 121 and 122 from the shaft 117, Fig. 11, when the clutch 120 is engaged and therefore the carrier bars 121 and 122 are arranged to receive movement from the shaft 117 in the course of a rotation thereof, the arrangement being such that a complete reciprocatory movement will be imparted to the carrier bars 121 and 122 upon each rotation of the shaft 117, the clutch 120 being of the type known as a one-revolution clutch and being operative to insure that the shaft 117 will make but a single complete revolution each time the clutch is engaged in a manner to be explained presently.

In the present instance reciprocatory movement is imparted to the carrier bars 121 and 122 through a lever 150, Figs. 8, 9, 10, 11 and 14. As best shown in Fig. 11, a stub shaft 151 projects upwardly from the bracket 111 and one end of the lever 150 is pivotally mounted on this stub shaft, a hub 152 unitary with the lever 150 being disposed about the stub shaft 151 and being rested on a bearing surface 153 on the bracket 111 whereby a bearing for the lever 150 is afforded about which said lever may rock. Also as best shown in Fig. 11, the portion of the lever opposite the end thereof whereat the hub 152 is provided is offset upwardly to terminate in a horizontal foot portion 154. This foot portion 154 supports a square block 155, Figs. 8, 10, 11 and 14, which is pivotally connected thereto, as indicated at 156, and which is supported to be slidable between the arms 128a and 128b of the bracket 128, the block 155 being slidable between these arms in the course of reciprocatory movement that is imparted to the lever 150 in the following manner.

A bevel gear 157, Figs. 9 and 11, is fast on the shaft 117 and meshes with a bevel gear 158 fast on the vertically extending shaft 159 that is journaled in suitable bearings in the bracket 111. An arm 160 is secured to the upper end of the shaft 159 and carries a slotted block 161, Figs. 10 and 11, in which the lever 150 is disposed, the rotative mounting of the arm 160 and the connection thereof to the lever 150 affording a Scotch yoke connection so that as the shaft 150 rotates, the lever 150 is reciprocated from the normal at rest position thereof shown in full lines in Fig. 10 to the broken-line position thereof shown in this view and then back to the aforesaid normal at rest position thereof, this being effected, as stated, in a single revolution of the shaft 117 upon engagement of the clutch 120.

The one-revolution clutch 120 is of the character shown and described in my copending application Serial No. 239,561, filed November 8, 1938, and includes a sleeve 162, Figs. 10 and 11, that is slidably, but non-rotatably, connected to the shaft 117, this sleeve having clutch teeth 163 formed on the inwardly disposed end thereof opposite complementary clutch teeth 164 provided on the hub 165 of the gear 118. A pin 166 on the sleeve 162 normally engages a cam surface 167 on an arm 168 that is pivotally mounted on a support rod 169 carried by the bracket 111, this arm 168 being spring-urged toward the sleeve 162, and so long as this pin engages this cam surface the clutch teeth 163 are held from engagement with the clutch teeth 164. A collar 162a rotatably mounted on the sleeve 162 is connected by a spring 163a to an adjoining cam disc 173, Figs. 11 and 14, which is secured to the shaft 117. This spring is normally effective to urge a pin 178 on the collar 162a into engagement with 75 a stop 179 carried by the arm 168. The pin 166

on the sleeve 162 is likewise normally engaged with this stop and is seated in a slight indentation formed in the adjacent edge of the collar 162a. The disc 173 includes a sharp drop 174, Fig. 14, that is engaged by a roller 175 on an arm 176, which arm is pivotally mounted on the support rod 169 and is acted upon by a spring 177. The spring 163a, Fig. 11, interconnecting the disc 173 and the collar 162a is placed under tension when the roller 175 seats in the drop 174 of the disc 173, as will be explained.

At predetermined times in the course of operation of the machine the solenoid 170, carried by an auxiliary bracket 171, Fig. 10, from the bracket 111, is energized and the armature 172 thereof is attracted, this armature carrying a lug which is engageable with the arm 168 so that upon energization of the solenoid 170 the arm 168 is pivoted about the pin 169, and the cam surface 167 and stop 179 are retracted from engagement with the pins 166 and 178. This leaves the spring 163a free to act upon the collar 162a, rocking this collar and causing the pin 166 to be cammed out of the aforesaid indentation in the collar and shifting the sleeve 162 along the shaft 117 until the clutch teeth 163 and 164 mesh, whereupon the shaft 117 is connected to the gear 118 for rotation therewith. When the shaft 117 and therefore the sleeve 162 have rotated a certain amount, the pin 166 momentarily engages and rocks the armature 172 (which is pivoted to the core of the solenoid 170), disengaging the lug thereon from the arm 168, and thereupon the arm 168 falls back into engagement with the periphery of the sleeve 162 so as to dispose the cam surface 167 in the path of the pin 166 which, near the end of a complete revolution of the shaft 117, rides up over the cam surface 167 to thereby disengage the clutch teeth 163 from the clutch teeth 164. A roller 168a carried by the arm 168 rides on the face of the gear 118 to prevent displacement of this arm when the clutch members are cammed apart.

As the shaft 117 nears the end of a complete revolution, the pin 178 on the collar 162a is arrested by the stop 179 and shortly thereafter the spring 177 acts through the arm 176 to urge the roller 175 down the sharp drop 174 in the cam disc 173, thus insuring that the shaft 117 will complete 360 degrees of rotation. The engagement of the pin 166 and stop 179 serves to prevent any overrunning of the shaft 117. Therefore, the lever 150 and the carrier bars 121 and 122 will be accurately disposed in their normal, at rest positions at the forward end of the stroke of the carrier bars, such positioning of the carrier bars being effective to dispose the printing and control devices in stations II to V, inclusive.

It will be manifest from the foregoing that a uniform reciprocatory movement is imparted to the lever 150 and therefore the carrier bars 121 and 122 each time the shaft 117 is set in operation and, as explained hereinabove, the forward stroke of the carrier bars 121 and 122 back to the normal at rest position thereof shown in Fig. 10 is slightly more than that required to advance a printing and control device from station II to station III. It has also been explained that the distance, for example, from station I to station II and from station III to station IV and from station IV to station V is less than the distance from station II to station III. However, the printing devices are advanced from one station to another and through unequal distances between these stations by the carrier bars in the

course of the uniform reciprocation imparted thereto. This is effected by properly spacing the printing and control device advancing pawls on the carrier bars 121 and 122 one from the other.

As best shown in Figs. 14 and 15 and 18 and 20, pawls 180 and 181 are respectively provided on the carrier bars 121 and 122 near the rear ends thereof. The particular disposition of these pawls along the extent of the respective carrier bars in which they are mounted, it being understood that these pawls are mounted in the respective carrier bars in transverse alignment one with the other, is so determined that when the carrier bars are retracted from the normal forward at rest positions thereof to the rearwardmost position thereof and thereafter these carrier bars are advanced from the rearwardmost position thereof back to the forwardmost normal at rest position thereof, the pawls 180 and 181 will, in the course of such forward movement of the carrier bars, engage the lowermost printing device in the magazine H at station I and will advance this printing device to station II, these pawls being effective to dispose this particular printing device in station II at the end of the forward movement of the carrier bars 121 and 122.

It will be appreciated that when a relatively large number of printing and control devices are stacked in the magazine H, appreciable downward force will be exerted on the lowermost printing and control device and as the lowermost device is advanced from the magazine, the next to the lowermost printing and control device, or what is to be the lowermost printing device, might be effective on the pawls 180 and 181 to depress these pawls from engagement with the rear edge of the printing and control device which should be advanced thereby. I have therefore so arranged these pawls that they are retained in position to be effective to engage the rear edge of the printing and control device that is to be advanced thereby when such a device is to be advanced thereby. Furthermore, for a purpose which will be explained hereinafter, there are times when the carrier bars 121 and 122 will be reciprocated but during which times it will not be desired to advance a printing and control device from, for example, station I to station II. I have, therefore, mounted the pawls as 180 and 181 in the carrier bars 121 and 122 in such a way that these pawls may be locked against downward displacement when the need so to do arises and also so that these pawls may be rendered ineffective to advance a printing and control device when the need so to do arises.

The manner in which the pawl 181 is mounted in the carrier bar 122 for the aforesaid purposes, and which is typical of the manner in which the pawl 180 is mounted in the carrier bar 121, is best illustrated in Figs. 21 and 22 and by referring thereto it will be seen that a notch or recess 183 is formed in the upper edge of the carrier bar 122 at the place whereat the pawl 181 is to be mounted therein. The rearward vertical wall of the notch 183 has a rounded recess 184 formed therein to receive a rounded projection 185 on the pawl 181 to thereby support the pawl for vertical movement in the recess 183. The forward wall of the recess 183 is shouldered as indicated at 186 to be engageable with a forwardly extending projection 187 at the lower part of the forward end of the pawl 181 to limit upward movement of the pawl in the recess 183.

In order to prevent displacement of the pawl 75 181 from the recess 183, a spring steel strip 188

is fast to the inwardly disposed face of the carrier bar 122, and this strip in cooperation with the adjacent face of the side plate 124 is effective to prevent displacement of the pawl 181 from the recess 190.

In Fig. 21 I have shown the pawl 181 in the position occupied thereby after this pawl has been effective to advance a printing and control device from station I to station II, the pawl remaining in this position until shortly before the bar 122 attains the rearwardmost position in the course of reciprocatory movement thereof for when this position is attained, the pawl 181 is moved into the position in which this pawl is shown in Fig. 22, the pawl being effective in this position to engage the rear edge of a printing and control device in station I and to advance this printing and control device to station II in the course of forward movement of the carrier bar 122.

By referring to Fig. 21 it will be seen that a pin 189 mounted in the strip 188 is disposed in a recess 190 formed in the lower edge of the pawl 181. In the course of rearward movement of the carrier bar 122, the strip 188 moves therewith and the pin 189 remains in the recess 190. However, shortly before the carrier bar 122 attains its rearwardmost position, the finger 191 engages the free end 192, Figs. 15, 21 and 22, of the spring 193 that extends across the printing and control device guideway G and which has the medial portion thereof secured to the bracket 194 pivotally mounted between the inner faces of the side plates 123 and 124, as best shown in Fig. 15. Adjustment screws 195 carried by the bracket 194 are effective on the spring 193 intermediate the point of securing thereof to the bracket 194 and the free ends thereof to dispose the end portions as 192 in adjusted positions to be effective on the finger 191.

The finger 191 projects downwardly from a rocker 196 that is pivotally mounted, as indicated at 197, on the carrier bar 122. The rocker 196 has a bifurcation 198 in the upper end thereof in which a pin 199 is disposed, the pin 199 being mounted in an adjacent portion of the strip 188. The strip 188 is slidably mounted in a recess as 200 in the inwardly disposed face of the carrier bar 122 and is retained therein by a plate 201 that is fast to the carrier bar 122 and which projects up over the strip 188, as shown in Fig. 22, this arrangement being effective to retain the rear end of the strip 188 against displacement from the recess 200. A finger 202, Fig. 22, secured to the carrier bar 122 projects across the open side of the recess 200 and is effective to retain the forward end of the strip 188 against displacement.

When in the course of the rearward movement of the carrier bar 122 the finger 191 on the rocker 196 engages the free end 192 of the spring 193, the rocker 196 is pivoted clockwise from the position in which it is shown in Fig. 21 into the position in which it is shown in Fig. 22 and when the rocker 196 so pivots, it is effective through the pin 199 to slide the strip 188 rearwardly in the recess 200 from the broken-line position thereof shown in Fig. 22 to the full-line position thereof shown in this view. Such rearward movement of the strip 188 retracts the pin 189 from the recess 190 into engagement with the lower edge of the pawl 181, which is thereupon pivoted upwardly so that the projection 187 thereon engages the shoulder 186, and such upward disposition of the pawl 181 disposes this pawl in position to engage the rear edge of the printing

and control device in station I upon forward movement of the carrier bar 122.

It will be understood that the pawl 180 is mounted in a manner similar to that hereinabove described with reference to the pawl 181 and hence by the time the carrier bars 121 and 122 attain their rearwardmost position, both the pawl 180 and the pawl 181 are disposed and are retained in a position to be effective to engage the rear edge of the lowermost printing and control device in station I, these pawls being disposed and retained in this position by the disposition of pins as 189 beneath the lower edges thereof in the manner illustrated in Fig. 22. Therefore, when the carrier bars 121 and 122 advance forwardly and the pawls 180 and 181 engage the rear edge of the printing device in station I, and as these pawls advance across station I into such a position that the weight of the remaining printing and control devices in the magazine H may be impressed thereon, the pins as 189 are effective to prevent depression of the pawls 180 and 181 which therefore remain in engagement with the rear edge of the aforesaid printing and control device until this printing and control device has been advanced to station II.

However, shortly before the printing and control device being advanced from station I to station II by the pawls 180 and 181 attains the position it is to occupy in station II, the finger 191 engages the stud 203 to be pivoted counterclockwise from the position in which it is shown in Fig. 22 into the position in which it is shown in Fig. 21, the finger 191 and the rocker 196 attaining this position after the printing and control device has been disposed in station II for when the printing and control device attains station II, the rocker 196 will have been so pivoted by the engagement of the finger 191 with the stud 203 that the strip 188 will have been moved from the full-line position thereof shown in Fig. 22 to the broken-line position thereof in this view. When the strip 188 is so moved, the pin 189 carried thereby is moved into alignment with the recess 190 in the lower edge of the pawl as 181 and when the pin 189 is aligned with the recess 190, this pawl may fall by gravity to the lower position thereof shown in Fig. 21, in which position it is ineffective to engage a printing and control device. It is the disposition of the pawl as 181 in this lowermost position that enables this pawl and therefore the corresponding pawl 180 to pass beneath the printing and control device in station I in the course of rearward movement of the carrier bars 121 and 122 so that these pawls will not be effective on the printing and control device disposed in station I until after these pawls have been disposed in the upper position thereof, in which position the pawl 181 is shown in Fig. 22, and the carrier bars 121 and 122 start to advance forwardly.

The foregoing arrangement for reciprocating the strip 188 in the recess 200 is of such a nature that the strip 188 and the parts operative therewith will remain in whichever of the above described alternate positions thereof these parts are disposed until they are forced into the other position by engagement of the finger 191 either with the free end 192 of the spring 193 or the stud 203, and in this respect, corresponding parts are effective on a strip corresponding to the strip 188 which is effective to dispose the pawl 180 in the lowermost and uppermost positions corresponding to the lowermost and upper-

most positions into which the pawl 181 may move, as hereinabove described.

Thus at the end of a forward movement of the carrier bars 121 and 122, the pawls 180 and 181 will be disposed in their lowermost positions and will be ineffective to advance a printing and control device from station I to station II unless and until the fingers as 191 engage the free end portions as 192 of the spring 193 and pivot the rockers as 196 from the position shown in Fig. 21 into the position shown in Fig. 22. In this respect reference has been made hereinabove to the fact that in certain reciprocations of the carrier bars 121 and 122 the pawls 180 and 181 are to be ineffective to advance a printing and control device from station I to station II. To this end the bracket 194 is mounted for pivotal movement between the side plates 123 and 124 by being mounted on a rod 204, Figs. 15 and 21, extended between the side plates 123 and 124. Furthermore, an opening 205, Fig. 19, is provided in the side plate 123 and a pin 206, fast on the adjacent arm of the bracket 194, extends through this opening and is connected to the armature 207 of a solenoid 208 that is carried by a bracket 209 secured to the side plate 123. A spring 210, Fig. 19, fast at one end to the side plate 123 and at the other end to the pin 206 is normally effective to urge the bracket 194 into the position in which it is shown in Figs. 21 and 22, the pin 206 engaging the upper edge of the opening 205 to dispose the bracket 194 in this position.

However, at a predetermined time in the operation of the machine, as will be described hereinafter, circuit is closed to the solenoid 208 to thereupon energize the same whereupon the armature 207 thereof is attracted downwardly against the effect of the spring 210. This is effective to dispose the bracket 194 in the broken-line position thereof shown in Fig. 22, whereupon the end portions as 192 of the spring 193 will be disposed in such position as to lie out of the path of the fingers as 191. Hence, when the solenoid 208 is energized and the carrier bars 121 and 122 are retracted from the forwardmost position thereof as, for example, from the position in which the carrier bar 122 is shown in Fig. 21 to the rearwardmost position thereof as shown in Fig. 22, the fingers as 191 do not engage the end portions as 192 of the spring 193 and therefore the bracket or rocker 196 remains in the position in which it is shown in Fig. 21, and consequently the pins as 189 remain in the recesses as 190, wherefore the pawls 180 and 181 are not moved to their upper positions in which they are effective to engage the rear edge of the printing and control device in station I upon forward movement of the carrier bars 121 and 122. Consequently, when the solenoid 208 is energized, the pawls 180 and 181 are ineffective to advance a printing and control device from station I to station II.

There will also be instances where the pawls 211 and 212, Fig. 15, which are effective to advance a printing and control device from station II to station III, are to be ineffective to so advance a printing and control device and consequently these pawls are so mounted to be movable between an upper effective position and a lower ineffective position. The manner in which the pawl 212 is mounted to enable this to be accomplished is shown in Fig. 22 where it will be seen that the pawl 212 is mounted in a recess 213, the vertical rear wall of which has a rounded recess 214 therein to receive a rounded projection 215

on the pawl 212. The pawl 212 also includes a projection 216 that is engageable with a shoulder 217 at the forward end of the recess 213. Moreover, a recess 218 is formed in the lower edge of the pawl 212 and a pin 219 carried by the strip 188 is movable to and from this recess 218 for the same purpose, in the same manner, and at the same time as the pin 189 is movable to and from the recess 190. It will be understood that the pawl 211 is mounted in a manner similar to the pawl 212 and also that the pawls 211 and 212 are mounted in transverse alignment one with the other.

Thus, when the shaft 117 is set in operation and the carrier bars 121 and 122 are moved from the forward normal at rest position thereof to the rearwardmost position thereof and the solenoid 208 is not energized, the fingers as 191 engage the end portions as 192 of the spring 193 and the strips as 188 are moved through the recess as 200 so as to move the pins as 189 and 219 out of the recesses as 190 and 218 into the positions thereof shown in Fig. 22, wherein these pins are effective to hold the pawls 180 and 181 in position to engage the rear edge of the printing and control device in station I upon forward movement of the carrier bars 121 and 122, and also to dispose the pawls 211 and 212 in position to engage the rear edge of the printing and control device in station II. It will be understood that this rearwardmost position of the carrier bars 121 and 122 is such that the pawls 211 and 212 are disposed immediately behind the printing and control device in station II, these pawls, at the end of such rearward movement of the carrier bars, however, being disposed beyond the rear edge of the printing and control device in station II only in an amount sufficient to insure that the pawls will be free to move up into position behind the rear edge of this printing and control device.

Therefore, as soon as the carrier bars start to advance forwardly from the rearwardmost position thereof, the pawls 211 and 212 engage the rear edge of the printing and control device in station II, and these pawls remain in engagement with the rear edge of this printing device until it is disposed in station III. However, by the time this printing and control device is disposed in station III the fingers as 191 will engage the studs as 203 and will have moved the strips as 188 so as to dispose the pins as 219 in alignment with the recesses as 218 and therefore the pawls 211 and 212 will be disposed in their lowermost position in which they are ineffective to engage the printing and control device in station II in the course of rearward movement of the carrier bars 121 and 122.

Furthermore, since the distance from station I to station II is less than the distance from station II to station III, the pawls 180 and 181 will not engage the rear edge of the printing and control device in station I at the time pawls 211 and 212 engage the rear edge of the printing and control device in station II. Rather, the pawls 180 and 181 will engage the rear edge of the printing and control device in station I at such time during the course of the advancing movement of the carrier bars 121 and 122 that, in the interval after the engagement of the pawls 180 and 181 with the rear edge of the printing device in station I and the time when these pawls are retracted to their lower or ineffective position, the printing and control device which has been in station I will have been advanced to station II. It will there-

fore be seen that while the carrier bars are effective to move the printing and control devices through the longest step required in the step-by-step advancing thereof, these carrier bars are also arranged to advance a printing and control device through a shorter distance.

In this respect it is to be noted that the distance from station III to station IV is materially less than the distance from station I to station II which, in turn, is less than the distance from station II to station III. Furthermore, in every reciprocation of the carrier bars 121 and 122, the printing and control device which has been in station III is to be advanced to station IV and therefore the pawls 220 and 221 which are effective to advance the printing and control device from station III to station IV are not arranged to be rendered ineffective upon energization of the solenoid 208. In this respect, however, it is to be noted that, whenever the solenoid 208 is energized, a printing and control device will not be advanced from station I to station II nor will a printing and control device be advanced from station II to station III, but in such circumstances a printing and control device is advanced from station III to station IV. Thus the pawls 220 and 221 are not respectively mounted in the carrier bars 121 and 122 in such a manner that they can be rendered ineffective to advance a printing and control device in the course of a reciprocation of the carrier bars 121 and 122.

Hence, the pawls 220 and 221 are respectively mounted in the carrier bars 121 and 122 in the manner illustrated, for example, in Fig. 18A where the pawl 221 is shown as mounted in the carrier bar 122, the pawl 220 being mounted in an identical manner in the carrier bar 121 in transverse alignment with the pawl 221. As shown in Fig. 18A, a pocket 222 is formed in the rearward upwardly extending wall of a recess 223 in the carrier bar 122 in which recess the pawl 221 is mounted, the pawl 221 including a rounded projection 224 on the rearward end thereof that is mounted in the pocket 222. A socket 221a is formed in the lower edge of the pawl 221 and a spring 225 is disposed in this socket and in an aligned pocket in the recess 223 and this spring is effective to urge the pawl upwardly into position to engage the rear edge of a printing and control device. A projection 226 formed on the forward end of the pawl 221 is engageable with a shoulder 227 formed in the forward upwardly extending wall of the recess 223 to thereby limit the upward movement of the pawl 221.

In the course of rearward movement of the carrier bars 121 and 122, the pawls 220 and 221 pass under the printing and control device in station III and in so doing are forced downwardly against the effect of springs as 225 and when these pawls have passed beyond the rear edge of the printing and control device in station III, the springs as 225 force these pawls into their upper effective position so that, in the course of forward movement of the carrier bars 121 and 122 in the reciprocation thereof, these pawls will be effective to engage the rear edge of the printing and control device in station III to thereby advance this printing and control device to station IV which, as explained hereinabove, is an intermediate station between stations III and V whereat impressions are made from the printing and control devices during the time the printing and control devices are disposed in these stations.

Another pair of pawls 228 and 229 are respec-

tively mounted in the carrier bars 121 and 122 forwardly of the pawls 220 and 221 and these pawls 228 and 229 are located in the carrier bars to be effective to advance a printing and control device from station IV to station V. Each of these pawls is mounted in the carrier bars in a manner similar to that in which the pawl 221 is mounted in the carrier bar 122, as described hereinabove, and these pawls are forced downwardly against the effect of springs similar to the spring 225, Fig. 18A, during the time they move under the printing and control device in station IV, but such springs are effective to dispose the pawls 228 and 229 in printing and control device engaging position once these pawls have passed beyond the printing and control device in station IV in the course of rearward movement of the carrier bars 121 and 122.

After an impression has been made from a printing and control device disposed in station V, this device is discharged into the throat 230, Fig. 18, of the printing and control device discharge chute, generally indicated by 231. In order to advance a printing and control device from station V into the throat 230, a pair of pawls 232 and 233 are respectively mounted in the carrier bars 121 and 122 in the manner in which the pawl 221 is mounted in the carrier bar 122, as described hereinabove, and in the course of rearward movement of the carrier bars these pawls pass beneath the printing and control device in station V and thereafter are urged into printing and control device advancing position by springs similar to the spring 225, Fig. 18A, to thereby be effective in the course of advancing movement of the carrier bars to move a printing and control device from station V into the throat 230.

A printing and control device discharged into the printing and control device discharge chute 231 passes through this chute and comes to rest in vertical position at the lower end of this chute so as to thereby be in a position to be returned to whichever one of the drawers J, Fig. 1, this printing and control device was stored in prior to the time such printing and control device was introduced into the magazine H, means suitable for effecting return of a printing and control device to the proper drawer as J from the position at the bottom of the printing and control device discharge chute 231 being described and claimed in my aforesaid copending application Serial No. 403,272, filed July 21, 1941.

It will be manifest that during the time pawls as, for example, 220 and 221 are passing beneath a printing and control device, these pawls are acted upon by springs 225, Fig. 18A, and therefore during the time such pawls are passing beneath a printing and control device they tend to urge such a device upwardly, and it is therefore essential that upward displacement of the printing and control devices from the carrier bars 121 and 122 be prevented, and it is otherwise advantageous to insure that the printing and control devices will be retained against displacement from the upper edges of the carrier bars 121 and 122. It will be understood that the inner faces of the side plates 123 and 124 are spaced apart sufficiently to enable a printing and control device of a predetermined width to be operatively fitted therebetween to enable passage of the printing and control device along the inner faces of these side plates. Furthermore, the upper edges of the carrier bars 121 and 122 are spaced downwardly from the upper edges of the side plates 123 and 124, as best shown in Fig. 11, to enable

the marginal edges of the printing and control devices to rest upon the upper edges of the carrier bars and at the same time to be slightly spaced beneath the upper edges of the side plates 123 and 124.

Hence, to prevent the aforesaid upward displacement of the printing and control devices from the upper edges of the carrier bars 121 and 122 and in order to define throats above the carrier bars through which the side marginal edges of the printing and control device may travel in the course of the advancing movement thereof through the printing and control device guideway G, strips 234 and 235, Figs. 11, 14 and 15, are respectively secured to the upper edges of the side plates 123 and 124 and, as best shown in Fig. 11, project inwardly beyond the inner faces of these side plates to thereby define the throats 236 and 237 in which the side marginal edges of the printing and control devices are disposed during the course of travel thereof through the guideway therefor.

During the time the printing and control devices are disposed, for example, in stations II, III and V, operations are performed thereon or under control thereof as, for example, when a sensing operation is performed thereon while the printing and control devices are disposed in station II and printing impressions are made therefrom when the printing and control devices are disposed in stations III and V. Moreover, it is essential that a printing and control device be retained in the intermediate station IV during the time, for example, the carrier bars 121 and 122 are moving rearwardly in the course of a reciprocation thereof. Particularly, however, when the printing and control devices are disposed in stations II, III and V, it is desirable that these devices be accurately positioned and to this end means are provided which are effective to accurately dispose and retain the printing and control devices in station IV.

In order that the printing plate 76 will be disposed accurately with respect to the platens as MP and PP when impressions are to be made therefrom and in order to insure that the coded perforations 85 will be accurately disposed with respect to the sensing means adapted to cooperate therewith in a manner to be described presently, such a plate and such perforations are accurately located on a printing and control device D with respect to a substantially V-shaped notch as 238, Fig. 4, provided in one marginal side edge of each device as D, and pawls including substantially V-shaped noses are provided in the machine for cooperation with these substantially V-shaped notches.

Thus, for example, a pawl 239, Fig. 14, is provided at station III in the machine, and this pawl is accurately located with respect to the platen MP. Therefore, since the printing plate 76 will be accurately located on a printing device D with respect to the notch 238 and since the pawl 239 is accurately located with respect to the platen MP, it is manifest that seating of the V-shaped nose 240 on the pawl 239 in the notch 238 in the printing and control device disposed at station III will insure accurate relationship between the printing plate on such printing and control device and the platen MP. It will be understood that since the notch 238 and the nose as 240 are substantially V-shaped they will so cooperate one with the other that in the event a printing and control device is not accurately disposed in station III, it will be shifted into an accurate posi-

tion by reason of the cooperation of these substantially V-shaped elements, this being in accordance with the arrangement described and claimed in Letters Patent No. 2,132,414, patented 5 October 11, 1938.

While it is advantageous to have a nose as 240 disposed to cooperate with a notch as 238 in order to insure accurate positioning of a printing and control device in a desired station as III and also 10 to insure that such a printing and control device will be retained in such a station until after an operation has been performed thereon or under control thereof, it is nevertheless desirable that a nose as 240 exert very little, if any, dragging friction on the side edges of the printing and control devices as D whereat notches as 238 are located for otherwise the nose 240 of a pawl as 239 might cause objectionable wear on the printing and 15 control devices. I have therefore so arranged the pawls as 239 that during the time the printing and control devices are being advanced by the carrier bars 121 and 122, a nose as 240 on such a pawl will bear very lightly upon the side edge of a printing and control device moving thereby so 20 as to thereby reduce wear incident to the passage of a printing and control device past such a nose to a minimum. It is essential, however, that when a printing and control device is disposed in such position that a nose as 240 may cooperate 25 with a notch as 238 therein, sufficient tension be applied to the pawl as 239 carrying the nose that the cooperation of the nose with the notch will bring about accurate positioning of the printing and control device, as explained hereinabove, and 30 also retention of the device in the desired position.

I have therefore so arranged the pawls as 240 in such a manner that but very light spring tension is impressed thereon during the time the printing and control devices are being so advanced and I have also so arranged these pawls that appreciable spring tension will be impressed thereon when the pawls are to be effective to dispose and retain a printing and control device accurately in one of the stations as III. In this 40 respect it is to be noted that a pawl 241, Fig. 19, similar to the pawl 239, is disposed to cooperate with a notch in a printing and control device disposed at station II. Furthermore, a pawl 242, Fig. 14, similar to the pawl 239, is disposed to cooperate with a notch in a printing and control device disposed at station IV, and still another pawl 243, Fig. 14, similar to the pawl 239, is disposed to cooperate with a notch in a printing and control device located at station V. It is on pawls such 50 as these that a relatively light spring pressure is impressed during the advancing movement of the carrier bars and on which relatively heavy spring tension is applied when these pawls are to be effective to accurately locate a printing and control device in the station with which the respective pawl is associated.

To this end a slot 244, Figs. 17 and 19, is formed in the outer face of the side plate 123 and a bar 245 is slidably mounted in this slot, this bar being retained in this slot by retaining members as 246, Fig. 17. Furthermore, a spring as 247, Fig. 17, is mounted on the side plate 123 in association with each pawl as 239 and the upper end of each such spring is passed through an 60 opening as 248, Fig. 14, in each pawl as 239. It will be noted that each spring as 247 is fast to the side plate 123 near the end thereof opposite that passed into the opening 248 by a screw as 249 or other suitable securing means. This arrangement is such that when the entire length of

each spring as 247 is effective on the pawl as 239 to which it is connected but very little tension is impressed on the pawl. In this respect it is to be noted that the spring 247a which cooperates with the pawl 243 at station V is somewhat shorter than other of the springs 247 but this spring 247a is made of lighter material than the other springs 247 so that it normally impresses substantially the same tension on the pawl 243 as that impressed on the other pawls by the other springs as 247.

However, when the pawls as 239 are to cooperate with a notch as 238 in the printing and control device D disposed at the station with which the particular pawl is associated, at which time, as explained, the spring tension impressed on the pawls is to be effective to shift the printing and control device into an accurate position, if necessary, and also to retain the printing and control device in this position, means are provided for increasing the tension of the various springs. To this end a finger as 250 is mounted on the bar 245 in operative association with each spring as 247, and each such finger includes a projecting portion that may be extended across each spring as 247 so as to, in effect, shorten the fulcrum about which the spring is effective. The fingers as 250, however, are only to be disposed in position to overlie the springs as 247 when the associated pawl is to cooperate with a notch as aforesaid for at all other times very light spring tension is to be impressed on the pawls.

Consequently, the bar 245 is arranged to be slidable longitudinally in the slot 244 so as to be movable between a position such as that in which it is shown in Figs. 17 and 19, wherein the fingers as 250 cooperate with the springs as 247, to a retracted position whereat these fingers are withdrawn from cooperating relation with the springs as 247.

Therefore, means are provided for shifting the bar 245 in the slot 244 and to this end a notch 251, Fig. 14B, is provided in the lower edge of the carrier bar 121 and another notch 252 is provided in the lower edge of this bar forwardly of the notch 251. These notches are arranged to define oppositely facing shoulders, the shoulder defined by the rear notch 251 facing forwardly and the shoulder defined by the front notch 252 facing rearwardly. An opening 253, Fig. 17, is provided in the side plate 123, and a pin 254, Fig. 14A, projects through this opening to be engageable in the notches 251 and 252. The pin 254 is fast in a finger 255 pivoted at 256 to the lower end of a plate 257 secured to the bar 245. A spring 258 extends between spring anchors respectively located on the side plate 123 and the finger 255 and acts on this finger to urge the pin 254 into engagement with the lower edge of the carrier bar 121.

In the latter part of the rearward movement of the carrier bar 121 the shoulder defined therein by the notch 252 engages the pin 254 and through the finger 255 and the plate 257 moves the bar 245 rearwardly and thereupon the fingers as 250 are retracted from the position in which they are shown in Fig. 17 so that the springs as 247 exert but slight tension on the pawls as 239, and the parts remain in this position throughout most of the forward movement of the carrier bars 121 and 122.

However, just before the carrier bars 121 and 122 attain their forwardmost position, the pin 254 enters the notch 251 and engages the shoul-

der thereof whereby as the carrier bars complete their forward movement the shoulder of the notch 251 acts through the pin 254, finger 255 and plate 257 to move the bar 245 forwardly, and in this movement the fingers 250 move into the position in which they are shown in Fig. 17 to thereby be effective to increase the tension of the springs as 247 since the effective length of the springs is thereupon decreased. Hence by the time the carrier bars 121 and 122 come to rest in the forwardmost position thereof, effective pressure is exerted by the springs as 247 on the pawls as 239 to thereupon bring about accurate positioning and firm retention of the printing and control devices in the stations into which they are moved in the course of the advancing movement of the carrier bars 121 and 122.

PLATENS

During the time the printing and control devices are disposed in stations III and V and effectively retained therein in the manner hereinabove described, impressions are made therefrom by the platens MP and PP respectively associated with these stations III and V, these two platens being mounted in spaced apart relation with each other to have the impression faces thereof aligned with the printing plate 76 on the printing and control device disposed in the station whereat the platen is arranged. Each of the platens MP and PP is hydraulically operated in the manner shown and described in my copending application Serial No. 416,548, filed October 25, 1941, now issued as Patent No. 2,410,935, patented November 12, 1946, and to this end a pair of pumps 259 and 260, Fig. 9, are provided. These pumps are carried by a bracket 261 that depends from the bar 137 that is fast to the rail 262, Fig. 8, of the frame F, the pumps 259 and 260 being connected to a cross rail 263, Fig. 9, of the bracket 261.

The pumps are set in operation at determined times in the course of operation of the machine, as will be explained in detail hereinafter, and to this end a pair of eccentrics 264 and 265, Fig. 9, are provided which are effective to reciprocate the pistons (not shown) of the pumps 259 and 260, these eccentrics being rotatably mounted on a shaft 266 journaled in the bracket 261. A gear 267 fast to the shaft 266 is meshed with a pinion 268 fast to the main drive shaft 90. Thus, whenever the main drive shaft 90 is in operation, the shaft 266 is rotated. The eccentric 264 is mounted on a sleeve 269 and the eccentric 265 is mounted on a sleeve 270, each such sleeve being disposed about the shaft 266.

Clutches of the character shown and described in my aforesaid copending application Serial No. 239,561, filed November 8, 1938, are provided for the purpose of connecting the sleeves 269 and 270 to the shaft 266 for rotation therewith, there being one clutch for each such sleeve. Each such clutch includes a collar fast to the shaft 266 which has clutch teeth thereon toward which clutch teeth on an adjacent end of the associated sleeve are normally urged. When the solenoid 271 of the clutch for the sleeve 269 is energized, this sleeve and therefore the eccentric 264 are connected to the shaft 266 to thereby set the pump 259 in operation, and similarly when the solenoid 272 is energized, the sleeve 270 and therefore the eccentric 265 are connected to the shaft 266 whereupon the pump 260 is set in operation, this arrangement being described in full

detail in my aforesaid copending application Serial No. 416,548.

A pipe 273 leads from the outlet of the pump 259 to the inlet 274, Fig. 8, of the cylinder 275 and when the pump 259 forces liquid through the pipe 273 into the cylinder 275 the piston 276 therein is forced downwardly whereupon the bar 277 extended between the spaced apart arms as 278 of the frame 279 of the main platen MP is forced downwardly, the frame 279 rocking about the knife-edged pivotal supports therefor as 280 to thereby bring the printing face 281 of the main platen MP into printing relation with type characters on the printing plate on a printing and control device retained in station III at a time when the main platen is thus rendered operative, the platen rocking in this operation against the effect of the spring 279a that is normally effective to maintain the platen MP in its upper ineffective position.

The main platen MP, in the present embodiment of my invention, is operated four times for each check as S that is printed in the machine. In the first two such operations of the main platen MP a printing and control device is disposed at station III and the printing face 281 of the main platen MP is therefore effective to make impressions from type characters T, on the printing plate of such printing and control device, onto the check S through the intermediary of, in the present instance, an inked ribbon (not shown). However, when the other two operations of the main platen MP are brought about, a printing and control device will have advanced from station III but a new or succeeding printing and control device will not have been moved into this station. When the main platen MP is rendered operative under such circumstances, the printing face 281 thereof is ineffective to make impressions on the check S. In such circumstances, however, the platens 282 and 283, Fig. 25, are rendered effective. The platen 282 is effective to make impressions through the inked ribbon from a numbering device 880 equipped with type wheels and which is described more fully hereinafter. The platen 283 is operable to make an impression through the intermediary of the aforesaid inked ribbon from the settable type bearing segments TS1 also described in detail hereinafter. In the first two operations of the platen MP, when the printing face 281 thereof is to be effective as described above, the platens 282 and 283 remain in the upper inoperative position in which these platens are shown in Fig. 25, these platens being carried by a support which is separate from the main frame 279, Fig. 8, of the main platen MP.

The support for the platens 282 and 283 includes the substantially rectangular frame 284, Fig. 24A, which has, at the rear end thereof, depending arms as 285, Fig. 25, that terminate in knife edges which are disposed in substantially V-shaped notches as 286 on the frame of the multiplying mechanism M described hereinafter. The frame 284 is normally supported in the upper position in which it is shown in Fig. 25 by a spring 287, Fig. 24B, that extends between a spring anchor 288, on the adjacent arm of the frame 279 of the main platen MP, and a spring anchor 289 on the frame 284. As best shown in Fig. 24C, a stud 290 extends outwardly from the adjacent arm of the frame 279 of the main platen MP and a latch 291 is pivotally mounted thereon. This latch, as best shown in Fig. 24B, has a shoulder 292 thereon that is normally disposed out of

alignment with the upper face of the frame 284. The latch 291 is normally disposed in the position in which it is shown in Fig. 24B where the inner face thereof above the shoulder 292 rests against the front edge of the frame 284 and in order to insure that the latch will remain in engagement with this edge of the frame 284, one end of a rod 293 is connected to the latch 291 and extends through a cross brace 293a in the frame 284. A head portion 294 is provided on the end of the portion of the rod 293 which extends beyond the cross brace 293a, and a spring 295 is disposed about this portion of the rod to extend between the cross brace 293a and the head portion 294. This spring is effective through the rod 293 to urge the latch 291 toward the front edge of the frame 284.

As will be explained more fully hereinafter with reference to the specific manner in which the check S is fed through the machine, a main cam shaft 300, Figs. 2, 24B and 41, is extended across the machine above the table top TT thereof that is carried by the frame F. This cam shaft operates in a determined timed relation with the various operative units in the machine and resort may therefore be had to cams on this cam shaft to control the latching of the frame 284 to the frame 279 of the main platen MP when the platens 282 and 283 are to be effective to make impressions onto the check S.

Thus, a cam 296, Figs. 24A and 24B, is fast on the main cam shaft 300 and a finger 297 depends from the rod 293 and is urged into engagement with the periphery of the cam 296 by the spring 295. Normally this arrangement is such that the engagement of the finger 297 with the cam 296 holds the latch 291 slightly forwardly of the front end of the frame 284. When, however, a drop on the cam 296 moves into alignment with the finger 297, the latch 291 is freed to the full effect of the spring 295 and at this time the frame 284 is lowered, in the manner explained presently, so that the shoulder 292 moves into engagement with the upper edge of the frame 284 and immediately thereafter, when the main frame 279 of the main platen MP is lowered, the platens 282 and 283 are moved into printing relation with the type members operatively associated therewith.

In order to bring about the aforesaid lowering of the frame 284 so as to enable the shoulder 292 to engage the frame 284 in the manner stated, a cam 298 is provided on the cam shaft 300 and an L-shaped member 299, fast to the cross brace 293a, has the foot portion thereon disposed beneath this cam. At a predetermined time in the course of a rotation of the cam shaft 300, a rise on the cam 298 moves into engagement with the foot portion of the L-shaped member 299 and thereupon this cam is effective to pivot the frame 284 about the knife edge on depending arms 285 thereof in an amount sufficient to enable the shoulder 292 to engage the upper edge thereof in the manner and for the purpose explained above.

The extent of the drop on the cam 296 which cooperates with the finger 297 on the rod 293 to free this rod to the full effect of the spring 295 is of sufficient length to enable the frame 284 to be moved with the frame 279 in the last two of the aforesaid four reciprocations of the frame 279 that are effected for making impressions on each check S. However, immediately after the fourth reciprocation of the frame 279 of the main platen MP, the drop on the cam 296 moves from

cooperating relation with the finger 297 and a rise on this cam is thereupon effective to move the shoulder 292 from cooperating relation with the upper edge of the frame 284 to thereby dispose the latch 291 in its aforesaid normal position in which it is ineffective to bring about movement of the frame 284 with the frame 279. In this respect it is to be understood that the rise on the cam 298 effective to depress the frame 284, so as to enable the shoulder 292 to engage the upper edge of the frame 284, need only be of sufficient length to bring about such downward pivoting of the frame 284 as will enable the shoulder 292 to engage the upper edge of this frame, and it will be appreciated that this rise on this cam 298 is so disposed thereon as to be effective to bring about the downward pivoting of the frame 284 at the proper time in the course of a complete cycle of operation of the machine. However, it will be apparent that as soon as the shoulder 292 has engaged the upper edge of the frame 284, this frame will remain latched to the frame 279 until the cam 296 effects disengagement of the shoulder 292 from the frame 284, as explained hereinabove.

While the main platen MP is operated four times in each complete cycle of operation of the machine, the proof printing platen PP makes but a single operation in a normal cycle of operation of the machine. This platen includes, however, a printing face 301, Fig. 24, that is effective to make impressions from type characters T on a printing plate on a printing and control device disposed at station V. The platen PP also is provided with a printing face 302 that is adapted for cooperation with the settable type carrying segments, generally indicated by TS2 and described in detail hereinafter. Furthermore, the platen PP is also equipped with a printing face 304 that cooperates with type bearing wheels on a numbering device, generally indicated by N2, that is described more fully hereinafter. In certain operations of the proof printing platen PP, all three printing faces 301, 302 and 304 thereof are to be effective to make an impression on the web W that is advanced through the machine by the pager and proofer mechanism PM.

In this respect it is to be noted that while the pager and proofer mechanism is generally of the character shown and described in my aforesaid copending application Serial No. 320,778, filed February 26, 1940, the web W that is advanced by this mechanism is not, in this machine, passed to the main platen MP, as shown and described in my just referred to copending application. Rather the web W is passed beneath the printing faces 301, 302 and 304 of the proof printing platen PP and is then directed back into the pager and proofer mechanism for the purpose of being divided into pages in the manner described in my last referred to copending application.

The web W is, therefore, led in the present machine from the pager and proofer mechanism PM beneath the three printing faces 301, 302 and 304 and about lower and upper guide rollers 306 and 307, respectively, Figs. 8 and 24, which are rotatably mounted in determined relation on a mounting frame 308 that is secured to the table top TT.

As best shown in Fig. 23, the printing faces 301, 302 and 304 of the proof printing platen PP are not mounted in alignment with each other for the printing face 301 which cooperates with type characters T, Fig. 4, on a printing and control device disposed at station V is disposed out of

transverse alignment with the printing faces 302 and 304 which are spaced forwardly of the upper arm 310 of the main frame 303 of the platen PP. The printing faces 302 and 304 are spaced forwardly of the printing face 301 in an amount equal to the distance the web W is advanced in each step-by-step movement imparted thereto by the feeding devices therefor in the pager and proofer mechanism PM, such means for advancing the web in a step-by-step manner being described in full detail in my aforesaid copending application Serial No. 320,778.

The effect of this arrangement is that in each printing operation of the platen PP variable data V are printed on the web W under control of data representations on a particular printing and control device but in this operation changeable data A, Fig. 3, are printed on the web W from type characters T on a different printing and control device. However, intermediate impression operations of the platen PP, the web W is advanced upwardly as viewed in Fig. 23 (rearwardly as viewed in Fig. 8) and such advancing brings the variable data V, Fig. 3, that are printed in a preceding operation of the platen PP into alignment but at one side of the printing face 301 and by this time the printing and control device, bearing the data representations under control of which the variable data V now aligned with the printing face 301 were printed, is moved into operative association with the platen PP whereby, upon the succeeding operation of the platen PP, the printing face 301 makes an impression onto the web W from type characters T on the printing and control device under control of data representations on which the variable data V now aligned with the printing face 301 were printed. Therefore, the variable data V and changeable data A, that are thus printed in alignment one with the other on the web W in different or succeeding operations of the platen PP, are related, which to say, these data are derived from the same printing and control device.

The printing face 302 is mounted on a projecting mounting plate 309, Fig. 24, carried on the main frame 303 of the upper arm 310 of the main frame of the platen PP. The printing face 302 is in fixed relation to the arm 310 and when the platen PP is operated through a printing stroke, the printing face 302 is lowered onto the top of the web W so as to act as a backup member against which the setup type on the type segments TS2 may be forced by the hammers associated therewith, as will be hereinafter described. When the type segments TS2 have not been set up, the lowering of the printing face 302 to such an operative position is ineffective to produce an impression on the web W inasmuch as blank portions on the type segments TS2 are disposed in operative relation with this printing face in these circumstances.

The printing face 301 is supported beneath the mounting plate 311 through the medium of a leveling plate 312, and this supporting means includes a plurality of expansive springs 313 which normally act to elevate the printing face 301 to such an extent that it is ineffective when the platen PP is actuated. In other words, when the printing face 301 is so retracted, the platen PP may be operated without producing a printing impression from a printing device located beneath the printing face 301. The printing face 301 is shiftable downwardly against the retracting force of the springs 313 by a pair of cam shafts 314 which are mounted transversely in the leveling

plate 312 so that the lowermost surface of the cam shafts 314 may be rotated into different engaging relationships with respect to the inner portions of the printing face 301 to move it into, or to permit it to move out of, its effective position depending upon the position of the cam shafts 314.

Thus when the cam shafts 314 are rotated into the position in which they are shown in Fig. 24, the printing face 301 is disposed in its effective position, but when these cam shafts are rotated clockwise, as viewed in Fig. 24, in a manner explained presently, flat portions 315 provided on the cam shafts 314 are brought into position above the printing face 301 thereby to allow the springs 313 to shift this printing face to its elevated or ineffective position.

The two cam shafts 314 are operated in unison by a pair of arms 316 which are connected to the cam shafts and which are also connected at their free ends to opposite ends of a link 317. One of the cam shafts 314 has an arm 318 projecting therefrom and at the end of the arm 318 a roller 319 projects beneath a downwardly facing abutment surface 320 formed on a depending arm 321. The arm 321 is, in the present instance, mounted on a cross brace 322 of the stationary frame 308. The arrangement of the arm 318 and the roller 319 is such that when the platen PP is being moved to its upward or retracting direction, the roller 319 strikes the abutment surface 320 so as to rock the cam shafts 314 in a counter-clockwise direction, as viewed in Fig. 24, thus shifting the printing face 301 to its lower or effective position. The printing face 301 is normally located in its effective position, and means is provided whereby during the first part of the printing stroke of the platen PP, the cam shafts 314 may be so rotated as to allow the printing face 301 to assume its ineffective position before the printing stroke of the platen PP is completed.

In the present instance the means for rendering the printing face 301 effective comprise a depending arm 323, Fig. 24, which is pivotally supported on the cross brace 322, and this arm 323 has a foot portion 324 which may be shifted into position beneath the roller 319 when the printing face 301 is to be rendered ineffective. The arm 323 is urged by a spring 325 to a position wherein its foot portion 324 is out of the path of movement of the roller 319, and when the printing face 301 is to be rendered ineffective, the arm 323 is shifted against the force of the spring 325 to an effective position wherein the foot portion 324 is beneath the roller 319. This end is preferably attained by means of a solenoid 327 mounted on the frame 308 and having its armature connected to the arm 323 by a link 328. When the solenoid 327 is energized, the foot portion 324 is rendered effective and in the course of the printing stroke of the platen PP, the printing face 301 is shifted to its ineffective position. In the upward or return stroke of the platen PP, the abutment face 320 operates to return the printing face 301 to its normal effective position. The solenoid 327 is energized for a purpose and in a manner described hereinafter with reference to operation of the machine.

The printing face 304 is supported on one end of an arm 330 which is pivoted as at 331 on the mounting plate 309, and the printing face 304 extends downwardly through a slot 332 formed in the mounting plate 309. The printing face 304 is normally urged into ineffective

position by a link 334 and a spring 335, the spring 335 being in surrounding relation to the link 334 so as to act between a stationary mounting rod 336 and an abutment means 337 provided on the upper end of the link. Thus when the platen PP operates through its printing stroke, the spring 335 maintains the printing face 304 in an ineffective position, and means is provided whereby the printing face 304 may be, in effect, locked to the mounting plate 309 to thereby be rendered effective so that an impression may be made thereby from the type wheels of the numbering device 881.

The means which are effective to lock the printing face 304 to the mounting plate 309 comprise a shiftable abutment member in the form of a rod 338 slidably mounted in upstanding mounting ears 339 and 340 fixed on the mounting plate 309. Intermediate the ears 339 and 340, the rod 338 carries an abutment disc 341 which may be shifted to a position wherein it overlies the arm 330. When the abutment disc 341 is so positioned, the arm 330 is locked in a predetermined position with respect to the mounting plate 309, and in the operative movement of the platen PP the spring 335 is compressed and does not cause the printing face 304 to be held in an ineffective position.

The rod 338 is actuated to bring the abutment disc 341 into its effective position by a solenoid 342 which is energized each time an impression is to be made by the printing face 304 in a manner and for a purpose described in detail hereinafter with reference to the operation of the machine. The solenoid 342 has its armature 343 connected to the rod 338 and a spring 344 acting on the armature 343 serves to return the rod 338 and the abutment 341 to their ineffective positions when the energizing circuit to the solenoid 342 is broken.

The platen PP is normally urged into an upper ineffective position by a spring 345, Fig. 24, and is urged into operative position against the effect of this spring when the pump 260 is rendered operative and forces liquid through the outlet pipe 346 leading from the outlet thereof to the inlet 347, Fig. 8, for the cylinder 348 in which the piston 349 is mounted. Fluid under pressure forced into the cylinder 348 by the pump 260 is effective to move the piston 349 through the cylinder 348 to be effective on the lower arm 350 of the main frame of the platen PP and forces this platen, or better, the aforesaid printing faces thereon, into printing relation with the type adapted for cooperation therewith.

In my copending application Serial No. 416,548, filed October 25, 1941, I have described in detail the manner in which the hydraulic systems of which the pumps 259 and 260 are a part are maintained filled with liquid at all times, and furthermore in that application I have explained in detail the manner in which the printing face as 281 of the main platen MP and, for example, the printing face 301 of the proof printing platen PP, may be adjusted to insure uniform printing thereof from type characters T moved into operative association therewith, and other details of the platens PP and MP are also fully described in this copending application to which reference may be had for a full description of such details.

Variable data as V1, Fig. 3, which in the present instance are the amount for which a particular check S is to be payable, and the variable data V2, which in the present instance are the number 75 of shares of stock determinative of the amount

of the variable data VI, are represented by perforations 85 in a printing and control device as D, Fig. 4, as explained hereinabove, and when the printing and control devices come to rest in station II, a sensing operation is performed on each printing and control device that comes to rest in this station to thereby, through a multiplying mechanism M, to be described presently, compute and set up in type segments the amount of the variable data VI for a particular check so that it may be printed on both the check as S and a proof sheet as, for example, PS1, Fig. 5, and means associated with the aforesaid multiplying mechanism are also effective to set up the number of shares of stock which in this instance will be the numerical value of the coded perforations 85 in a particular printing and control device.

Furthermore, there will be instances where, in a series of printing and control devices, there will be certain printing and control devices from which an impression is not to be made when this printing device passes through the machine so that, as described in the art, such a printing device will be skipped. The determination as to whether or not an impression is to be made from a particular printing device is known in the art as selection and this is effected by what is commonly known as a selector. The present machine is equipped with a selector that is operative to determine from each printing and control device whether or not impressions are to be made therefrom. This selector includes detecting means that cooperate with each printing and control device as it comes to rest in station II.

In order that the selector included in the machine may determine whether or not impressions are to be made from a particular printing and control device in the course of passage thereof through the machine, identifying means are provided on the printing and control devices D and in the present instance a tab TB is provided on the printing and control device, Fig. 4, this tab being connected to the printing and control device in a selected position thereon to impart a particular identification to the printing and control device in the manner, for example, shown and described in Letters Patent No. 2,049,436, patented August 4, 1936.

VARIABLE DATA DETECTING MEANS

In an instance where as in the present instance numerical data V are represented by perforations in a printing and control device as D and these perforations are to be formed in the printing and control device in accordance with the code shown in Fig. 4A, perforations may appear at any one of five positions to represent the significant digits, zero being indicated by the omission of a perforation. Furthermore, the present machine is responsive to representations of numerical data in as many as five digital orders. Therefore, the area on the printing and control device whereat perforations may be formed is of such size that coded perforations may be produced at any one or more of five positions in any one or more of five transversely related rows on the printing and control device D.

Inasmuch as the data representing perforations may be formed in any one or more of five positions in any one or more of five different rows, I provide five rows of sensing pins as 351, Fig. 20, in the detector head generally indicated by 352, there being five pins as 351 in each of the five rows thereof. These pins are so located in the detector head 352 that when a printing and con-

trol device is retained in station II, in the manner described hereinabove, the twenty-five pins as 351 will be respectively aligned with the twenty-five positions on the printing and control device whereat perforations may be formed. The arrangement is such that when the detector head 352 is lowered, in a manner to be explained presently, those pins 351 which are aligned with perforations in the printing and control device pass through such perforations, but those pins which come into engagement with an unperforated area on the printing and control device rest against the face of and are prevented from moving into cooperation with means that are adapted to cooperate with the pins 351 upon passage thereof through a data representing perforation in a printing and control device.

The means which so cooperate with pins as 351 that pass through a coded perforation are mounted in a block 353 disposed between the side plates 123 and 124 of the printing and control device guideway and which is secured thereto. This block has a plurality of openings 354 therein which, like the pins 351, are arranged in five rows with five openings in each row, and these openings 354 are respectively aligned with the pins 351 so that when a pin 351 passes through a data representing perforation in a printing and control device located at station II, such pin may move into engagement with a pin 355 disposed in the opening 354 aligned with the particular pin 351.

As best shown in Fig. 20, an anchoring plate 356 is secured to the underside of the block 353 and this plate has a plurality of openings therein respectively aligned with the pins 355 and the openings 354 and the sheathings about Bowden cables as 357 are respectively fast in such openings in the plate 356 so that the Bowden cable enclosed in each such sheathing may be extended into engagement with the head at the lower end of the aligned pin 355. Therefore, when a pin 351 moves into engagement with a pin 355, by reason of the fact that the pins 351 are spring-urged into a position to extend beyond the head 352, as best shown in Fig. 20, such pin 351 is effective to push the particular Bowden cable aligned with the pin 355 engaged by a pin 351 that has passed through a perforation in a printing and control device at station II. When a Bowden cable is pushed in this manner, such a cable, in cooperation with other similarly pushed cables, if any, is effective, in a manner to be explained presently, to enter into the multiplying mechanism M one factor of the to be performed multiplications and in the present instance such factor is the number of shares of stock owned by the person or the like to whom the particular printing and control device at station II pertains, which is to say, the person or the like identified by the type characters T on the printing plate 16 on this particular printing and control device.

In this respect, each row of pins as 351, as such a row appears in Fig. 20, pertains to one digital order of the variable factor of the to be performed multiplications, there being, therefore, in the present instance five rows of pins, which rows respectively pertain to the units, tens, hundreds, thousands and ten thousands orders inwardly from the side plate 123, as viewed in Fig. 15.

Furthermore, in accordance with the code shown in Fig. 4A, when any one of the odd digits 1, 3, 5 and 7 is represented, two perforations as 85 are provided and two pins as 351 in the particular row pass therethrough to thereby push two

cables in the row thereof aligned with such pins. When the even digits 2, 4, 6 or 8 are to be represented, one such cable is pushed in this manner. When the digit 9 is represented only the one cable is pushed, this being the cable which is pushed along with some other cable when one of the odd digits 1, 3, 5 or 7 is represented.

Thus depending upon the number of orders into which a numerical amount represented by perforations as 85 in a printing and control device D extends and depending upon what digits are represented in each digital order of such order, one or more Bowden cables as 357 are pushed. This is effective, in the present instance, to set up control means in the multiplying mechanism M representative of the digital value in each digital order in which perforations as 85 appear in a printing and control device at station II so that representations of such digital values are set up to control setup of a digit representing arrangement in the multiplying mechanism M pertaining to the particular digital order of the variable factor (the multiplier in this instance) in a multiplication to be performed by the multiplying mechanism M, this arrangement being described in further detail hereinafter with reference to the multiplying mechanism M.

The detector head 352, in which the pins 351 adapted for cooperation with the Bowden cables 357 are mounted, is disposed between and secured to a pair of interconnected arms 400 and 401, Figs. 19 and 20, which, at the rear ends thereof, have depending arms as 402 and 403 that are pivotally connected, as indicated at 404 and 405, to the side plates 123 and 124, respectively, in such position as to dispose the pins as 351 in the detector head 352 in alignment with the openings 354 in the block 353, Fig. 20. When the pins 351 are to effect a sensing operation on coded perforations as 85 on a printing and control device D located at station II, the arms 400 and 401 are pivoted about the pivots 404 and 405 therefor to bring the pins into such a sensing position, and suitable means are therefore provided for effecting such pivotal movement of the arms 400 and 401.

Inasmuch as the detecting pins 351 are to be moved toward the coded perforations as 85 in a printing and control device D at station II, only after such a printing and control device has come to rest in this station to be retained therein in the manner described hereinabove, and since the sensing pins 351 must be maintained in an upper ineffective position, in which they are shown for example in Figs. 19 and 20, during the time the printing and control devices are being advanced from one station to another, there is an operative interrelation between the advancing of the printing and control devices and the operation of the detector including the detector pins 351 and the arms 400 and 401. Hence, I operate the detector from means included in the means operative to advance the printing and control devices. To this end a pair of conjugated cams 406 and 407, Figs. 11 and 12, are provided. These cams are mounted on a common hub 408 fast to the shaft 117 and are effective to retain the detector in the upper position in which it is shown in Figs. 19 and 20 and they are also effective to lower the detector into sensing position when the need so to do arises.

The conjugated cams 406 and 407 are respectively engaged by rollers 409 and 410 respectively mounted at the free ends of the arms 411 and 412

of a bifurcated rocker 413 fast on the shaft 414, Figs. 12, 13 and 14, journaled in bearings 415 in the bracket 111 and the bracket 113. A rocker 416, Figs. 10 to 14, inclusive, is also fast on the shaft 414 and carries a boss 417, Figs. 10 and 14, in which one end of a rod 418 is pivotally mounted. The opposite end of the rod 418 is passed through a suitable opening in a bracket 419, Figs. 15 and 19, fast to the side plate 123 of the printing and control device guideway G, and is adjustably connected in a block 420 pivotally connected, as indicated at 421, to a rocker as 422 pivotally mounted, as indicated at 423, Fig. 19, on the side plate 123. The rocker as 422 has an elongated slot as 424, Fig. 19, therein in which a roller as 425 disposed on the arm 401 is mounted.

The conjugated cams 406 and 407, Fig. 11, are effective through the bifurcated rocker 413, Fig. 12, to rock the shaft 414 and therefore the rocker 416 which, through the rod 418, block 420 and rocker as 422, is effective to elevate and lower the detector including the sensing pins 351, these parts being effective, when the conjugated cams are in the position shown in Fig. 12, to hold the detector in the upper elevated position in which it is shown in Figs. 19 and 20 and also being effective during the course of a rotation of the shaft 117 to bring about lowering of the detector pins 351 toward a printing and control device in station II, retained therein in a manner described hereinabove. This reciprocation of the detector including the pins 351 is effective to push those Bowden cables 357 that are aligned with pins 351 that pass through coded perforations in the printing and control device at station II as described.

SELECTOR

Reference has been made hereinabove to the determining of whether or not impressions are to be made from the printing and control devices as they pass through the machine and also to determining whether or not other operations are to be effected from or under control of the devices. This, as has been stated, is effected through the medium of what is commonly referred to in the art as a selector. In the present instance the detecting portion of such a selector is associated with the detecting pins 351 and embodies a pin as 426, Figs. 19 and 20, mounted in the detector head 352. What is commonly referred to as a selector bar, indicated by 427 in Fig. 20, is removably secured to the arms 428 and 429 that are mounted above the arms 400 and 401 in a manner explained presently.

In accordance with the usual practice, the selector bar 427 has openings therein in alignment with the positions whereat tabs TB, Fig. 4, are disposed when a printing and control device is located at station II, there being, on the printing and control devices, a plurality of positions whereat the tabs TB may be selectively secured. In the present instance an opening is provided in the selector bar in alignment with each half of the upper portion of a tab as TB so that by cutting away one-half of such a tab only the remaining half thereof will be effective, for so to do doubles the number of selector positions afforded by tabs as TB on a printing and control device as D, this also being in accordance with well-established practices in the art. Then when some particular selector position is to be rendered effective, a plug is inserted into the opening at this position in the bar 427 and a pin as 426 is mounted in the head 352 in a corresponding selected position. In such an event, when the detector head

352 is lowered in a manner hereinabove described and the pin as 426 engages a tab TB, the pin as 426 is effective to move the selector bar 427 and the parts in which it is supported in a manner to be described presently. If, however, the pin as 426 does not engage a tab as TB, then the bar 427 remains in the position in which it is shown in Fig. 20 and the arms as 428 and 429 are not moved relative to the arms 400 and 401.

Selections are made in the present instance in dependence upon whether or not the arms as 428 and 429 are pivoted relative to the arms 400 and 401 and resort is had to such a selection in an instance, for example, where dividend checks are being prepared, because of the fact that some shareholders of corporations desire to have dividend checks, payable to them, sent to some particular bank. On the other hand, the printing and control devices that are passed through the present machine may also be utilized for the purpose of preparing proxy notices and the like, and when such proxy notices are to be prepared they are sent to the respective shareholders rather than to banks designated by shareholders for receipt of payments of dividends.

In instances such as this, two printing and control devices are provided for each shareholder who desires to have dividend checks payable to him sent directly to a bank to be deposited to his account, and one such printing device has type characters as T embossed thereon for the purpose of printing changeable data on the check to enable the foregoing to be accomplished. However, each such shareholder is also provided with another printing and control device on which type characters as T are provided for the purpose of printing changeable data which will cause proxy notices and the like to be sent directly to the shareholder. Each such printing and control device included in a series thereof which is for the purpose of printing changeable data on a check or the like to be payable to a bank has a tab TB (or a half tab as explained) fast therein in a selected position thereon, while each printing device which is intended for the purpose of addressing proxy notices and the like has a tab TB (or a half tab as explained) fast thereon at a different position. It will be understood that all printing and control devices in the series that are to be used for the purpose of printing checks as aforesaid have tabs as TB secured thereon in an identical position, and this also applies with respect to those printing and control devices adapted for printing proxy notices and the like.

When the printing and control devices in a series thereof are tabbed as aforesaid and it is desired to print checks, in which instance it will not be desirable to print from those printing and control devices adapted for printing proxy notices and the like, a pin as 426 is mounted in the head 352 in a position to cooperate with tabs (or half tabs) on those printing and control devices adapted for the preparation of proxy notices and the like, and a plug is inserted in the opening in the selector bar 427 in alignment with this pin. Furthermore, when proxy notices are to be printed, a pin 426 and a plug in the selector bar 427 as aforesaid are disposed in position to cooperate with tabs on those printing and control devices which are adapted for the production of checks. Then, depending upon with whichever ones of the aforesaid two tabs (or half tabs) the aforesaid pin and plug are aligned, when the series of printing and control devices are passed through the machine, those printing and control devices

bearing tabs which are engaged by the pin are, in the nomenclature of the art, skipped, which is to say, they are passed through the machine without having a printing impression made thereon and without having other operations performed thereon or under control thereof save the selecting operation. It will be understood that all printing and control devices which do not have a tab in position to engage the pin as 426 are in such circumstances utilized in printing and other operations in the machine.

It is to be understood that, if desired, more than one pin as 426 could be provided in a particular setup of the machine so that tabs in more than one position on the printing and control devices could be effective for the purposes above described, but in any event when a pin as 426 cooperates with a tab, the arms 428 and 429 are pivoted upwardly about the pivotal supports as 430, Figs. 19 and 20, therefor, these bars being urged toward such supports by springs as 431 and 432, Figs. 19 and 20. Supports as 433 and 434 are rabbed at the upper edges thereof to receive the arms 428 and 429 and support the same in their normal position, and this arrangement is such that when a pin 426 engages a tab as aforesaid, the arms 428 and 429 are pivoted upwardly relatively to the supports 433 and 434 about the pivotal supports as 430.

It will be understood that the arms 428 and 429 are connected together for conjoint movement when such arms are pivoted upwardly as described, and such conjoint movement of the arms 428 and 429 is utilized in the present instance to operate switches which in turn control electrical circuits so as to thereby control the operation of operative mechanisms in the machine in a manner described more fully hereinafter. In this respect it is to be noted that this electrical arrangement is of such a nature that the effect of upward pivoting of the arms 428 and 429 may be utilized either for the purpose of skipping printing and control devices as aforesaid or for causing such printing and control devices to be printed to thereby, in effect, reverse the operation of the selector, this particular arrangement also being described in detail hereinafter with reference to the particular switches which are controlled by upward pivoting of the arms 428 and 429.

In the present instance a switch pile, generally indicated by 435, Fig. 19, is mounted on the side plate 123 of the printing and control device guideway and the switches of such pile include leaves that are extended over pins as 436 of insulating material that are mounted in a plate 437 on the arm 428. It will therefore be seen that whenever a pin as 426 engages a tab as TB (or a half tab as explained) the switches in the switch pile 435 are operated, and the manner in which this is utilized in the course of operation of the machine is described in detail hereinafter.

It will be understood that a detecting operation is made on each printing and control device which advances to station II and therefore each printing and control device which advances to this station and which has coded perforations as 85 therein will enable Bowden cables as 357, Fig. 20, to be pushed. Furthermore, as will be explained presently, the Bowden cables as 357 are effective to set up controls in the multiplying mechanism M to the extent that operative devices in the multiplying mechanism M, in the course of an operation of this mechanism, cooperate with the control afforded by the pushed of the Bowden cables to determine the result of an operation of

the multiplying mechanism M which, in the present instance, is the computation of a product and the setting up of type segments from which variable data VI may be printed and also, as will be explained, type segments from which variable data as V2 may be printed.

However, even though the Bowden cables as 357 are pushed in each detecting operation, the multiplying mechanism M is not necessarily set in operation to utilize the setup effected by pushing of the Bowden cables 357 because operation of the multiplying mechanism M is under control of the selector including the switches in the switch pile 435 which are operated in the manner explained above. However, because the Bowden cables are thus pushed in each sensing operation, an arrangement to be described presently is provided for effecting restoration of the Bowden cables to their normal at rest position in the course of operation of the machine so as to insure that these Bowden cables and the parts connected thereto will be disposed in a normal at rest and ineffective position at the initiation of each detecting operation.

Thus, irrespective of whether or not the multiplying mechanism M is to be set in operation the Bowden cables as 357 are pushed in the sensing operation so that in the event the multiplying mechanism is set in operation it will function in response to data representations on the printing and control device which is thus sensed. Therefore the Bowden cables 357 in each set or row thereof as viewed in Fig. 20, are led from the anchor plate 356, Fig. 20, at detecting station in the machine, to another anchor plate included in the multiplying mechanism M, as will be explained presently.

MULTIPLYING MECHANISM

The multiplying mechanism M disclosed in the accompanying drawings is generally of the character shown and described in my aforesaid copending application Serial No. 313,146, filed January 9, 1940, and in the present instance is of the character utilizing what is referred to in that application as a reoccurring factor. Thus, in the present instance, where the machine is to be used for the purpose of preparing dividend checks, the dividend rate will remain constant for a particular dividend to be paid and, therefore, the amount for which each check as S is to be payable may be determined by multiplying this dividend rate, or reoccurring factor, by a variable factor, the number of shares of stock of the corporation owned by the person to whom the check as S is to be payable.

In this respect it is to be understood that, if desired, resort could be had to the universal multiplying mechanism disclosed in my aforesaid copending application Serial No. 313,146 without departing from the purview of the present invention. Moreover, more than one reoccurring factor could be incorporated in the multiplying mechanism M in the manner shown and described, for example, in my aforesaid copending application Serial No. 313,147, filed January 9, 1940, and the particular reoccurring factor that is to be effective in a particular operation of the multiplying mechanism M could be selectively rendered effective in the manner described, for example, in my last referred to copending application. In addition to the foregoing, there are certain aspects of the multiplying mechanism M, as disclosed in the accompanying drawings that are primarily described in my aforesaid copend-

ing application Serial No. 313,147, and furthermore there are certain structural changes embodied in the present multiplying mechanism over and above the arrangement shown and described in my aforesaid copending applications Serial Nos. 313,146 and 313,147, these structural changes being described in detail hereinafter.

Moreover, as has been explained hereinabove, the representations of numerical values are afforded in the printing devices as D, Fig. 4, by coded perforations as 85 and such values may extend through as many as five digital orders. The present machine is arranged to enable such a five-digit variable factor to be multiplied by a five-digit reoccurring factor, but it is to be understood of course that the number of digits in each of the factors is a matter of selection and may be varied as desired.

However, where resort is had to a reoccurring factor, as explained hereinabove, a set of templets as TP, Fig. 37A, are grouped together in what may be referred to hereinafter as a templet-gang TG and, in accordance with the manner described in detail in my aforesaid copending applications Serial Nos. 313,146 and 313,147, digit representing steps are afforded in the templets TP in each templet-gang TG to represent all of the digits that may be ascertained when a particular reoccurring factor is multiplied by the digits of a notation, and the arrangement being such that these digit representing steps afford representations of what is referred to hereinafter and in my aforesaid copending applications Serial Nos. 313,146 and 313,147 as an intermediate product.

To facilitate definition of the terms used in connection with the description of the multiplying mechanism M included in the present machine, the following example of the multiplication of 99999 by 99999 is set forth, this being the largest multiplication that may be effected within the capacity of the mechanism where accommodation is afforded for five digital orders in the multiplicand and in the multiplier, this example being as follows:

99999	Multiplicand
99999	Multiplier
899991	First intermediate product
899991	Second intermediate product
899991	Third intermediate product
899991	Fourth intermediate product
899991	Fifth intermediate product
9999800001	Final product

For the purpose of the present description, the reoccurring factor is considered to be the multiplicand and the multiplier is considered to be the variable factor, that is, the factor derived from the coded perforations as 85 in the printing and control devices as D. When the reoccurring factor or the multiplicand is multiplied by all of the digits in a notation, what are referred to in the above example as intermediate products are ascertained. The aforesaid templets TP in each gang are arranged to embody aligned steps as TPS which respectively represent the digital values pertaining to the respective orders of the final product which are ascertained when the reoccurring factor is multiplied by a digit appearing in a particular order of the multiplier the steps as TPS, for example, for the digit 1 in the multiplier being arranged in transverse alignment on the various templets in a templet-gang as TG,

and this applies with respect to other digits that may appear in the particular order of the multiplier to which the particular templet gang pertains.

The templets TP are arranged in the templet-gangs TG in such a way that each templet in the gang is operatively associated with means related to the order of the final product to which the particular digits represented pertain. Thus, in the foregoing example, the digit 1 which relates to the units order of the final product when 99999 is multiplied by 9 in the units order of the multiplier is so arranged in the machine as to be operatively associated with means pertaining to the units order of the final product, and this applies with respect to the other digits in the intermediate product ascertained in the course of the aforesaid multiplication. Furthermore, and in accordance with the foregoing example of longhand multiplication, the templets TP in the templet-gang pertaining to the tens order of the multiplier are so related to the templets in the templet-gang for the units order that the templet relating to the first ascertained factor in the course of a multiplication by a digit appearing in the tens order of the multiplier is operatively associated with the templet relating to the tens order of the product ascertained in the course of a multiplication of the reoccurring factor by the digits in the units order of the multiplier. This same arrangement is resorted to for each other templet in each templet-gang so that means related to the respective orders of the final product may operate to summarize digital values operatively associated therewith and which, therefore, relate to the order of the final product to which the particular summarizing means pertains. A carry-over mechanism of the character described, for example, in my aforesaid application Serial No. 313,146 is effective to transfer from a lower order to the next higher order any carry-overs which arise in the course of such a summarizing operation since each one of the aforesaid summarizing means is capable of representing only the digit that is to appear in the order of the final product to which such summarizing means pertains.

It will be seen from the foregoing that, where there is a reoccurring factor in the to be performed multiplications and templets are included in templet-gangs as TG to represent intermediate products as aforesaid, representations of all of the intermediate products that may be ascertained upon multiplication of the reoccurring factor by the digits that may appear in any order of the variable factor or multiplier are represented in a single templet-gang. Therefore, a templet-gang as TG is provided for each order of the variable factor, there therefore being in the present instance five templet gangs TG which respectively relate to the units, tens, hundreds, thousands and ten thousands orders of the variable factor or the multiplier, such templet-gangs being generally indicated in Fig. 25 as TG-U, TG-T, TG-H, TG-TH and TG-TT.

It has been explained hereinabove that each row of Bowden cables as 357, as such a row is viewed in Fig. 20, is led to an anchor plate in the multiplying mechanism M and to this end the 70 row of Bowden cables 357 which are pushed upon the passage of pins 351 through perforations as 85 relating to the units order are led to an anchor plate operatively associated with the templet-gang TG-U, and similarly the rows of 75 as 442 connected thereto are pushed being de-

Bowden cables respectively related to the tens, hundreds, thousands, and ten thousands orders are led to anchor plates respectively associated with the templets TG-T, TG-H, TG-TH and TG-TT. Thus, in Fig. 37A, wherein the templet gang TG-TH is shown, the Bowden cables as 357 which are pushed when pins as 351 pass through one or more perforations as 85 in the thousands order of a numerical value represented on a printing and control device located at station II are led to an anchor plate 438 wherein the sheathings about the aforesaid Bowden cables are firmly anchored against displacement.

There is an anchor plate as 438 for each templet-gang TG and these anchor plates are secured to a bar 460 to be respectively aligned with the templet-gangs TG, the bar 460 being supported by brackets as 461 which, in turn, are connected to a bar 462 that is secured to, but spaced from the side plate 378, of the multiplying mechanism M, the side plates 377 and 378 of this mechanism being spaced apart to support the templet-gangs TG and associated mechanisms therebetween. As best shown in Fig. 37A, the bar 462 is supported by studs 463 to be disposed in spaced relation with the adjacent face of the plate 378. The bar 460 is also supported by posts as 439 which are secured to the side plate 378 in the manner illustrated, for example, in Fig. 37A.

An arm as 440 is journaled for pivotal movement in the bar 462 in alignment with each templet-gang as TG and has a boss 443 at the lower end thereof and five vertically aligned openings are provided in the arm 440 and boss 443 for the reception of five pins as 442. The Bowden cables as 357 are extended between the anchor plate as 438 and are respectively fast to the pins 442 so that when one of the Bowden cables as 357 is pushed, the pin connected thereto is pushed to be disposed in front of steps PS on the positioning templet PT, there being one such positioning templet for each templet-gang TG and, as best illustrated in Fig. 37A, each such positioning templet is disposed on the outer face of the side plate 378, this arrangement being described in full detail in my aforesaid copending applications Serial Nos. 313,146 and 313,147.

The various steps PS on the positioning templet PT are operative to dispose the steps as TPS on the templets TP in operative association with sensing means disposed between the side plates 377 and 378 of the multiplying mechanism and, depending upon what digit is represented by pushed of the pins 442 steps TPS representative of the digital values in the intermediate product ascertained when the digit represented by pushed of the pins 442 is multiplied by the reoccurring factor, are disposed in cooperative relation with the aforesaid sensing means, this arrangement being described in full detail in my aforesaid copending application Serial No. 313,146.

Reference has been made hereinabove to the fact that Bowden cables as 357 are pushed each time a sensing operation is effected on a printing and control device at station II and such printing and control device has coded perforations as 85 therein, and reference has also been made to the fact that such Bowden cables are restored to a normal at rest position intermediate the time they are pushed in one sensing operation and the time they are to be pushed in the succeeding sensing operation, the particular time at which the Bowden cables as 357 and the pins 442 connected thereto are pushed being de-

scribed hereinafter with reference to operation of the machine as is the time at which restoration of such Bowden cables to the normal at rest position is effected.

However, in order to effect restoration of the Bowden cables and the pins 442 to their normal at rest positions, a restoring plate 441 is mounted on each set of Bowden cables 357 intermediate the pins 442 and the anchor plate 438, this plate 441 having a bifurcation therein through which such Bowden cables are passed. Collars as 465 are fast on the Bowden cables adjacent the restoring plate 441. Furthermore, a bifurcated arm as 466 has the Bowden cables 357 disposed in the bifurcation therein, this arm being disposed between the pins as 442 and each restoring plate as 441. The arm 466 is pivotally mounted on a rod as 467 carried by blocks 468 in the posts 439. A lever 469 is fast to the rod 467 and has a link 470 pivotally connected thereto at the free end thereof. The link 470 is also pivotally connected to the armature 471 of a solenoid 472 carried by a bracket 473 from the side plate 378.

When restoration of pushed of the Bowden cables 357 is to be effected, the solenoid 472 is energized in the manner described hereinafter and thereupon the rod 467 is pivoted counter-clockwise, as viewed in Fig. 37A, to move the arms as 466 into a vertical position in engagement with the associated restoring plate 441, and collars as 465 on the Bowden cables as 357 that have been pushed are engaged by the restoring plate 441 in the course of movement of the arm 466 into the aforesaid vertical position so as to thereby insure restoration and disposition of all Bowden cables as 357 and pins 442 associated therewith in their proper normal at rest positions.

The multiplying mechanism M is set in operation subsequent to the time pins as 442 have been selectively pushed. When the multiplying mechanism is so set in operation pins as 474, Fig. 37B, are retracted from engagement with the positioning templets PT to thereby free these positioning templets, and the templet gangs of which they are a part, to the effect of springs as 475 and thereupon the steps PS on the particular positioning templet PT are moved into engagement with the pushed of the pins 442 to thereby dispose the representations, afforded by the steps TPS, of the proper intermediate product in operative association with the sensing means described presently. The pins as 474 are secured in a slide bar 476, Fig. 37B, mounted on the outer face of the side plate 378 for slidable movement which is imparted thereto from a rocker 477, Fig. 37B, that has a link connected thereto which, in turn, is operated by a cam included on the main cam shaft 499, Fig. 26, of the multiplying mechanism M, such releasing and positioning of the templets under the effect of springs as 475 being described in detail in my aforesaid copending application Serial No. 313,146.

The multiplying mechanism M includes a plurality of plates as 358, Figs. 28 and 29, each of which respectively pertains to an order of the final product and since in the present instance the final product may extend through ten orders, ten such plates 358 are provided between the side plates 377 and 378, this arrangement being in accordance with that described in my aforesaid copending application Serial No. 313,146.

A plurality of sensing fingers as 359, 360, 361, 362 and 363 are mounted on each plate as 358

to be movable toward the digit representing steps TPS that are disposed in operative position when the templet gangs are freed to the effect of the springs 475, as explained above. The plate 358 is typical of various plates that are included in the present machine and this plate is equipped with five sensing fingers as aforesaid because this particular plate relates to the thousands order of the final product and therefore five templets TP will be provided for this order in an instance where the capacity of the mechanism is such as to care for the multiplication of a five-order number by a five-order number. In instances, however, where there will not be as many as five templets for the particular order of the final product, as in the case of the units order of the final product, only as many sensing fingers as 359 are provided to be effective on the plate relating to such order of the final product, this also being in accordance with the arrangement described in my aforesaid copending application Serial No. 313,146.

In the present instance all of the templet-gangs TG are mounted along the upper edges of the side plates as 377 and 378 in the manner best shown in Fig. 37A. Therefore all of the sensing fingers as 359 to 363 on a plate as 358 are arranged to move upwardly. These sensing fingers are interconnected by what is, in effect, a rectilinearly moving planetary gear train such as described in my aforesaid copending application Serial No. 313,146. To this end a sensing finger as 359 has a pinion as 364 rotatably mounted thereon in position to engage a rack on a rack slide respectively disposed on each side thereof as the rack slides 365 and 366 are disposed on opposite sides of the pinion 364 on the sensing finger 359. Because all of the sensing fingers are arranged to extend upwardly, I interpose between adjacent sensing fingers an idler pinion as 367 which, in the present instance, meshes with a rack on the rack slide 366 and with another rack on the rack slide 368 associated with the sensing finger 360 in the manner in which the rack slide 365 is associated with the sensing finger 359.

Each sensing finger is connected, through a pinion mounted thereon and rack slides mounted adjacent thereto and an intermediate pinion 367, to each other sensing finger. The last of the sensing fingers as 363 carries a pinion as 369 which meshes with a rack on a rack slide 370 which, in turn, has a rack that meshes with a pinion as 371. This pinion is engaged by a retaining device as 372 effective to hold it against undesired rotation. The retaining device and pinion 371 afford an adjustment for, when the retaining device is retracted from engagement with the pinion 371, the planetary gear train may be moved into, for example, its normal zero indicating position and then the retaining device 372 is engaged with the pinion 371 to thereby assure that the summation means including the aforesaid fingers, pinions and rack slides, will be disposed in a normal at rest position when this is to be effected.

In order to minimize friction incidental to movement of the sensing fingers as 359 and the rack slides as 365, relative to the plate as 358, a thin shim as 450 is fast to the plate 358 to underlie each idler gear as 367, and an opening 451 is provided in this shim about the idler gear as 367, a washer as 452 being disposed between the adjacent face of the plate 358 and the idler gear to thereby reduce friction of the idler gear relative to the plate 358. As best shown in Fig. 30, the rack slides as 366 and 368 only have the me-

dial parts thereof engaged with the outwardly disposed face of the underlying shim 450, whereby the main extent of these slides is free of the adjacent face of the plate 358. In view of the fact that each pinion as 364 on each finger as 359 overlies the adjacent edges of the shims as 450 on each side thereof, as shown in Fig. 30, this pinion in each finger as 359 is held away from the adjacent face of the plate 358.

A summation member as 375 is associated with each plate as 358 and is connected to the planetary gear train on such plate through a pinion as 374 and a rack on the adjacent rack slide as 365. The pinion 374 is rotatably mounted on a slide as 373 which, as best shown in Fig. 28, projects to the face of the plate 358 opposite that on which the pinions as 364 and rack slides as 365 are mounted. The slide 373 cooperates with digit representing steps on a carry templet of a carry-over mechanism which is of the character described in my aforesaid copending application Serial No. 313,146.

Springs as 376, Fig. 25, extend between the lower ends of the summation members as 375 and a bail 453, Fig. 25, and these springs are effective on the summation members in such a way as to place the planetary gear train associated therewith under tension to thereby eliminate backlash in this gear train to insure accurate summarizing of the digits represented by steps TPS on templets TP aligned with the sensing fingers as 359 associated with each particular summation member as 375.

As described in detail in my aforesaid copending application Serial No. 313,146, in the course of operation of a multiplying mechanism as M the bail 453 is lowered and thereupon the springs 376 are effective to move those summation members 375 downwardly which have sensing fingers as 359 associated therewith that are aligned with steps TPS on templets TP representative of significant digits, and in the course of such lowering of the summation member as 375 the sensing fingers as 359 move into engagement with the aligned steps and thereupon the digital values represented by the steps TPS are summarized. The summation member 375 comes to rest in position to represent the digit that is to appear in the order of the final product to which the summation member 375 pertains, any carry-overs that may be encountered in the course of such a summarizing operation being transferred through the above referred to carry-over mechanism to the next higher order.

It will be understood that as soon as all of the sensing fingers as 359 have engaged templet steps TPS, then the particular summation member 375 associated therewith comes to rest and any further downward movement of the bail 453 is merely effective to elongate the particular spring 376 connected to this summation member. Hence, when the summation members as 375 come to rest at the end of a summarizing operation, these summation members respectively represent the digits which are to appear in the order of the final product to which each member respectively pertains. This setup of the summation members is utilized in the present instance for the purpose of setting up type segments from which a product so ascertained may be printed and also, in a manner to be explained presently, the products so ascertained are entered into an accumulating arrangement wherein the totals hereinabove referred to are accumulated so as to enable

such totals to be printed when so desired, this being explained hereinafter.

Inasmuch as the illustrated multiplying mechanism M has a capacity of multiplying a five-order number by a five-order number, capacity is afforded for setting up ten different type segments. However, I have found that in the preparation of dividend checks the amounts which are usually paid pursuant to such checks usually do not exceed seven orders of which two pertain to cents and the remainder to dollars. Therefore, in the present machine, I do not utilize all ten summation members as 375 for the purpose of setting up type segments for I have provided but seven type segments, as will be described presently for the purpose of printing variable data as V1, checks as S and proof sheets as PS1.

Furthermore, in the preparation of dividend checks, dividend rates such as twelve and one-half cents are sometimes encountered and in such instances the checks are made payable only in cents so that, for example, in an instance where the dividend rate is .12125 there will, in effect, be three orders to the left of the units order in the cents. Hereinabove, I have referred to the summation members as 375 and the plates as 358 associated therewith as respectively pertaining to the orders of the final product and the lowermost of such plates normally pertains to the units order of the to be performed multiplications. In instances where the dividend rates do not include fractions of a cent, the lowermost, that is, the one of the summation members 375 which pertains to the units order of the final product, is utilized for the purpose of setting up type segments for printing the units order on a check. In the instance where the dividend rate is, for example, .12125, the fourth from the lowermost summation member as 375 is utilized for the purpose of setting up the type segments which prints the units order of cents and the three summation members below this particular summation member are merely utilized as summarizing means to enter over into the summation member, that is to be effective to set up a type member for the units order of cents, those fractional cent amounts that are accumulated in the aforesaid three lowermost summation members as 375.

It will therefore be seen that the multiplying mechanism M is capable of being utilized either to have whole or fractional cents multiplied thereby and yet at the same time this mechanism may be utilized for setting up type segments effective only to print full cents in the units order of cents on a check, and that this may be done in an accurate manner by reason of the fact that carry-overs from lower orders or, in other words, the fraction of a cent will be entered into the summation member which is effective to set up the type segment that is utilized to print cents. The foregoing may be accomplished for the reason that the type segments that are set up under control of the multiplying mechanism are not directly connected thereto but are rather connected thereto through the intermediary of Bowden cables, as will be described presently.

In this respect, however, it is to be noted that the summation members as 375, in the course of a summarizing operation thereof, may be called upon to move through a distance which, in effect, will be representative of 25, in which instance, of course, the digits appearing in the tens order of an amount as 25 is transferred to the 75 summation member for the next higher order.

However, in the course of the advance of the sensing member such as 375 into a position to be representative of 25, it will pass through positions representative of two and one-half notations, that is to say, through positions representative of the values 0 to 9, 10 to 19 and 20 to 25, in the instance where a summation member comes to rest in a position representative of 25. The summation member is, however, utilized to set up the 5 in the units order of an amount as 25 and, therefore, an arrangement somewhat similar to that shown and described in my aforesaid copending application Serial No. 313,147, filed January 9, 1940, is provided for the purpose of enabling the digital amount, which a summation member as 375 is set up to represent, to be ascertained.

SETUP OF VARIABLE DATA PRINTERS

The setup of the variable data printers is effected from the summation members as 375 and to this end a strip as 480 is fast to one face of each such summation member. Each such strip is formed to provide a plurality of shoulders as 481—U, 481—T and so on, the shoulder 481—U being effective to represent the digits in the notation from 0 to 9, the shoulder 481—T being effective to represent the digits in the units order of the notation from 10 to 19, the shoulder 481—H being effective to represent the digits in the units order of the notation 20 to 29 and so on. Thus when a summation member as 375 comes to rest at the end of a summarizing operation thereof, one of the shoulders 481 thereon will be disposed in a digit representing position which, in the present instance, is related to the at rest position of the finger as 482, Fig. 26, it being understood that there is one such finger for each summation member as 375 that is to be utilized for the purpose of setting up type segments in the manner that will be described presently.

As best shown in Fig. 26, the finger 482 is provided on a slide 483, which is retained in engagement with the plate as 358, that pertains to the particular summation member 375 with which the finger 482 is adapted to cooperate, by a guide 484 disposed near the upper edge of the plate 358 and by another guide as 485 provided near the lower edge of the plate. The guide 485 is in the form of a grooved roller movable in the vertical slot 486 in the slide as 483 and therefore the slide 483 is capable of vertical movement relative to the plate as 358.

A rod 487 extends between the side plates 377 and 378 of the multiplying mechanism M and has a plurality of levers as 488 mounted thereon, there being one such lever for each slide 483. Each such lever 488 carries a roller 489 mounted for movement in the slot as 490 in the slide 483 with which the lever 488 is associated. A plurality of springs as 491 are effective on the levers as 488 and normally tend to urge the fingers as 482 toward the shoulders as 481 on the strips as 480 but are restrained from so doing by engagement of the levers 488 with a bail 492 that is pivotally mounted on the rod 487. This bail has a depending arm 493 to which one end of a link 494 is pivotally connected, the opposite end of this link being pivotally connected to a lever 495 pivotally mounted, as indicated at 496, in the multiplying mechanism M between the side plates 377 and 378. A roller 497 on the lever 495 is urged toward a peripheral cam 498 on the cam shaft 499 of the multiplying mechanism M by a spring 482a effective on the link 494.

In the course of operation of the multiplying

mechanism M the cam shaft 499, Figs. 24C, 25 and 26, makes a complete revolution under control of a one-revolution clutch of the kind, for example, shown and described in my aforesaid copending application Serial No. 239,561, filed November 8, 1938. In the course of such rotation of the cam shaft 499 the cam 498, through the roller 497, so pivots the lever 495 that, through the link 494 and arm 493, the bail 492 is retracted from the position in which it is shown in Fig. 26 into a position such as that in which the springs 491 may be effective through the levers 488 to urge the fingers as 482 toward the strip as 480 and the shoulders as 481 thereon associated therewith. This particular operation will occur at a time in the course of operation of the multiplying mechanism M after the summation members as 375 have been disposed in digit representing positions as aforesaid. As a result of the foregoing, the finger as 482 is positioned for cooperation with whichever one of the shoulders 481 is to be effective, and immediately after the finger 482 has been moved into this cooperating relation it is caused to engage whichever one of the shoulders 481 with which it is to cooperate in the particular operation in progress, it being the engagement of the fingers as 482 with the positioned shoulders as 481 that disposes the type segments, referred to hereinabove and described hereinafter, in position to print whatever digits are represented by the positioned shoulders 481.

Therefore, immediately after the cam 498, Fig. 26, has enabled the fingers as 482 to move as just described, the cam 500, Fig. 35, on the cam shaft 499 enables the slides as 483 to effect engagement of the fingers as 482 carried thereby with the positioned of the cooperating shoulders 481. To this end a roller 501 follows the periphery of the cam 500. This roller is mounted on the rocker 502 that is fast on the shaft 503 journaled in the main side members 504 and 505 of the multiplying mechanism M between which side frame members the side plates 377 and 378 are mounted to be supported therefrom. The rocker 502 includes an arm 506, Fig. 35, and another rocker arm 507 is fast on the shaft 503 outwardly of the side plate 378, the arm 506 being disposed outwardly of the side plate 377. The rocker arms 506 and 507 respectively have links 508 and 509 pivotally connected at the free ends thereof, and these links carry a bar 510 which extends across toe portions as 511, Fig. 26, on each of the slides as 483, springs as 512 being effective on these toe portions to normally urge the toe portions upwardly into engagement with the rod 510. The rod 510 passes through slots as 513 in the side plates 377 and 378 to be movable in these slots. Therefore, when the cam 500 through the roller 501 actuates the rocker 502, the rocker arms 506 and 507 elevate the rod 510 which moves away from the toe portions as 511 and thereupon the slides 483 are freed to the effect of the springs as 512 to be urged upwardly, as viewed in Fig. 26. When the slides 483 are freed to the effect of the springs as 512, the fingers as 482 engage the positioned of the shoulders as 481 to thereby dispose the slides as 483 in digit representing positions, each such slide 483 being disposed in position to represent whatever digit is represented by the positioned cooperating summation member 375. The type segments which are set up from the positioned slides 483 and which are effective to print the variable data as VI on the checks as S and the proof sheets as PSI are dis-

posed in two groups TS1 and TS2, Figs. 24, 24C, 26 and 27, and are selectively settable simultaneously, these type segments being set up through the intermediary of devices also described presently, which, in turn, are set up from the slides as 483.

With respect to the shoulders as 481 moving into digit representing positions and also with respect to the manner in which the fingers as 482 cooperate therewith, the digit representing position attained by the summation members as 375, and therefore the shoulders as 481, with respect to the fingers as 482 is such that if a shoulder 481—U is disposed in a position to be representative of the digit 9 in a summarizing operation, it will be disposed in position such that when the finger 482 moves inwardly, in the manner above described, this finger will so cooperate with the shoulder 481—U that when the slide 483, on which such finger 482 is carried, is freed to the effect of its spring 512 upon elevation of the rod as 510, only operative clearance will be taken up between the finger 482 and the shoulder 481—U. Such cooperation of the sensing finger 482 with a shoulder 481—U is attained, as will be hereinafter explained in detail, by imparting an initial upward movement to the sensing fingers 482 prior to the actual sensing movement thereof, thereby to place the sensing fingers in initial positions that are in effect one unit above the zero positions thereof. However, if the particular summation member 375 does not move downwardly in a summarizing operation, which will occur whenever each of the sensing fingers as 359 associated therewith cooperates with digit representing steps on the associated templets representative of zero, the shoulder 481—U will be disposed in such position that when the finger 482 moves upwardly, upon upward sensing movement of the rod 510, the associated slide 483 will move from the aforesaid initial position through what amounts to nine digit representing stations to thereby assume a position representative of zero. It will also be understood that if the shoulder 481—U is disposed in a position to be representative of one of the digits 1 to 8, in such an event the finger 482 and consequently the slide 483 will move until the finger 482 engages the shoulder 481—U and in so moving the slide 483 will attain a position representative of whatever digit is represented by the positioned and cooperating shoulder 481—U.

Furthermore, when the shoulder 481—T moves into a position representative of the zero in the numerical value of 10, the finger 482 and therefore the slide 483 moves through nine digit representing stations, and this slide moves through whatever number of spaces may be required to represent the digits in the units order of the values 11 to 18, but when the shoulder 481—T is in a position representative of the 9 in 19, then here again the finger 482 moves only sufficiently to take up operative clearance between the finger 482 and the shoulder 481—T. The taking up of operative clearance between the finger 482 and a shoulder 481 has no digital significance so that the slide 483 is disposed in a digit representing position after such clearance is taken up. The foregoing description also applies with respect to other of the shoulders 481 for it will be recognized that such shoulders only represent the value that appears in the units order of whatever value is represented by the position of the summation bars as 375 on which the particular shoulders 481 are provided.

Thus since the slides as 483 are disposed in digit representing positions when the rod 510 is moved upwardly from engagement with the toe portions 511 thereon, the positions in which such slides are so disposed may be utilized to set up the type segments in groups thereof as TS1 and TS2, Figs. 24, 24C, 26 and 27, and in the present instance such positioning of the slides is utilized to set up such type segments through the intermediary of Bowden cables as will be described presently.

In the present instance the groups of type segments TS1 and TS2 are mounted forwardly of and substantially in alignment with the multiplying mechanism M, and therefore the summation members as 375 and the slides as 483. Resort is had to this arrangement because it is convenient so to do in view of other constructional characteristics in the present machine. However, since groups of type segments as TS1 may be set up from the slides as 483 through the intermediary of Bowden cables, it will be understood that type segments of this character could be located at any position in the machine that might be required to produce impressions at desired positions on sheets as the check S and proof sheets as PS1 and to which Bowden cables could be conveniently extended.

In the present instance, however, Bowden cables as 515, Figs. 26 and 26A, lead from arms as 516 on rockers as 517 that are mounted on a rod 518 extended between and carried by the side plates 377 and 378, the rockers as 517 each including an arm as 519 having a pin as 520 thereon disposed beneath a foot portion as 521 on a particular one of the slides 483. In a manner explained presently, the Bowden cables as 515 are pushed substantially simultaneously with the setting up of the slides as 483 into digit representing positions. Therefore, the positions in which the Bowden cables as 515 are disposed is controlled by the digital position in which the associated slides as 483 is disposed, the Bowden cables, therefore, also assuming digit representing positions.

In the present instance, each Bowden cable as 515 is connected to a slide as 522, Figs. 26 and 26A, the ends of the sheathing about said cables adjacent said slides being fast in an anchor plate 515a therefor that extends between and is fast to the main side frame members 504 and 505. The slides 522 are mounted for vertical movement in combs as 523 and 524 that extend between and are carried by the side frame members 504 and 505, as best shown in Fig. 26A. It will be understood that it is slides as 522 that are located in association with the desired or required location of the type segments to enable set up of the type segments to be effected.

Each slide as 522 has a rack as 527 thereon with which is meshed a gear segment as 528 on a rocker as 529. As best shown in Fig. 26A, each rocker as 529 is mounted on a shaft 530, extended between and carried by the side frame members 504 and 505 and which is journaled in bearings 526 therein. Collars as 529a, Fig. 26A, are disposed between the rockers 529 to align these rockers respectively with the racks as 527 on the slides as 522.

A gear segment as 531 on each rocker as 529 is respectively engageable with the teeth of pinions as 532 that, as described more fully herein-after, are effective when disengaged from the gear segments as 531 to dispose positioning slides as 555 in digit representing positions from which these slides subsequently move, as described here-

inafter, to dispose the type segments in the groups TS1 and TS2 in position to print the proper digits as determined by the operation of the multiplying mechanism M. The pinions as 532 engage racks as 554 on the positioning slides 555 to be effective to dispose these slides in digit representing positions, there being one such slide for each pinion as 532.

To enable the pinions 532 to be disposed in digit representing position and to enable these pinions to dispose the slides 555 in digit representing positions, the pinions 532 are mounted on a shaft 533 which, in a manner explained presently, is arranged for vertical movement so that the pinions may be demeshed from the racks as 554 and meshed with the associated gear segments 531 or, conversely, so that these pinions may be demeshed from the gear segments 531 and meshed with the racks 554. To this end the shaft 533 on which the pinions 532 are rotatably mounted in suitably spaced apart relation is extended through vertically extending slots as 534, Fig. 25, in the side frame members 504 and 505 to be guided for vertical reciprocation in these slots. Such vertical reciprocation of the shaft 533 is imparted thereto from cam slots as 535, Fig. 26, formed in cam plates 525 and 526 that are pivotally mounted on the shaft 530. The cam slots are of such configuration that when the cam plates 525 and 526 are pivoted clockwise, as viewed in Fig. 26, and into the position shown in this view the shaft 533 is caused to move upwardly to demesh the pinions 532 from the gear segments 531 and to mesh these pinions with the racks 554, the cam plates 525 and 526 moving counterclockwise, as viewed in Fig. 26, to move the shaft 533 downwardly and thereby demesh the pinions 532 from the racks 554 and mesh these pinions with the gear segments 531. In this respect, the teeth of the pinions 532 do not completely demesh from the teeth of the gear segments 531 until they are partly meshed with the teeth of the racks 554 whereby any digital settings into which the pinions 532 are moved, in a manner described presently, is retained.

The aforesaid clockwise and counterclockwise movement of the cam plates 525 and 526 is imparted thereto, in the present instance, from a cam 546 on the cam shaft 499 of the multiplying mechanism M through the intermediary of a lever 543 that is pivotally mounted on a shaft 544 that extends between and is journaled in suitable bearings in the side frame members 504 and 505. A spring 547 is effective on this lever to urge a roller 545 thereon into engagement with the periphery of the cam 546. A roller 542 on the other end of the lever is disposed in a bifurcation in a lug 541 that depends from the cam plate 526 and under control of the configuration of the cam 546, the movement of this roller in this bifurcation effects the aforesaid rocking of the cam plates 525 and 526, these cam plates being interconnected at the lower ends thereof by the rod 539, Figs. 26 and 26A.

A spring as 548, Fig. 26, extends from a spring anchor 548a to each of the rockers 529 that include the gear segments 531 and 528, and these springs normally urge the rockers 529 clockwise, as viewed in Fig. 26, to thereby be effective to urge the slides 522 downwardly. Since the slides 522 are connected through the Bowden cables 515 with the rockers 517 and since these rockers include pins 520 which respectively engage toe portions 521 on the slides 483, it is manifest that when the bail 510 moves upwardly to free the

slides 483 to the effect of the springs 512 each of the rockers 529 is free to pivot in an amount determined by the digital position assumed by the slide 483 with which it is connected through the intermediary of the Bowden cable as 515 and devices associated therewith. Therefore, since the pinions as 532 will be meshed with the associated gear segments 531 on the associated rockers 529 at the time the bail 510 moves upwardly, it is manifest that the pinions 532 will be disposed in digit representing positions, upon upward movement of the bail 510, that are respectively related to the digit positions assumed by the slide as 483 to which the pinions 532 are respectively interconnected through the intermediary of the devices including the rockers 529, Bowden cables 515 and rockers 517.

In a manner explained presently, each pinion as 532 is disposed in an initial position representative of 9 at the time the rockers 529 move under the effect of the springs 548, and in connection with the description of the operation of the mechanism, attention is directed to Figs. 26C and 26D which diagrammatically illustrate the parts 20 in association with appropriate scales so as to enable the relative movements of the parts to be readily understood. If, therefore, slide 483 is disposed in a position representative of 9 (which does not result in movement of the slide 483, as explained hereinabove), the pinion 532 meshed with the gear segment 531 on the rocker 529 connected to such slide 483, through a particular Bowden cable 515 and associated mechanisms, 25 does not move and remains in its initial position 30 that is representative of 9. If, however, the particular slide 483 has moved into a position representative of a significant digit other than 9, then the pinion as 532 moves into a position to represent such significant digit. In the event the 35 slide 483 moves to a position representative of zero, the pinion as 532 is also moved into a position to be representative of zero.

Each pinion as 532 includes twenty teeth to thereby be capable of representing the digits in 45 two notations but only one set of ten teeth is used in each operation of each pinion. A pair of thickened teeth as 550 are provided on each pinion 532 at what may well be called the two zero positions thereon. Each such thick tooth 550 is 50 adapted for cooperation with a tooth of a comb 551 mounted on a plate 538 that is pivotally supported, as indicated at 540, between a pair of plates 536 and 537, Fig. 26A, carried by the shaft 533 but held from rotation thereabout by a lug 536a that has a bifurcation that embraces the 55 shaft 530 on which the rockers 529 are pivotally mounted. A spring as 532 is effective on the plate 538 near the upper edge thereof to urge this plate toward an adjustment screw 553 mounted on an arm 554b, Fig. 26A, that extends over the rear face of the plate 538 at one side edge thereof from the cam plate 525. In the course of movement of the cam plates 525 and 526 from the position thereof shown in Fig. 26, the screw 553 tends to move away from the plate 538 and thereupon the spring 552 retracts the teeth of the comb 551 out of cooperating relation with the thick teeth 550.

However, when the cam plates 525 and 526 move clockwise, as viewed in Fig. 26, the cam slots 535 therein are effective to move the shaft 533 upwardly to thereupon mesh the teeth of the pinions 532 with the teeth of the racks 554 on the associated slides 555. In the course of this movement the adjustment screw 553 is effective

on the plate 538 to so move the comb 551 as to dispose the teeth thereof in position to respectively cooperate with the thick teeth 550. In order to limit rocking movement of the plate 538, an opening 540a is formed in one arm thereof into which a pin 540b, carried by the plate 536, projects and the engagement of this pin with opposed edges of the opening 540a disposes the plate 538 in the alternative operative positions thereof.

Subsequent to the meshing of the pinions 532 with the racks 554, the slides 555 are freed to the effect of springs and are thereupon operative to dispose the type characters on the type segments TS1 and TS2 in printing position, as will be explained. Those pinions 532 which are disposed other than in a zero position, which is the position thereof wherein a thick tooth 550 thereon engages a cooperating tooth on the comb 551, rotate counter-clockwise, as viewed in Fig. 26, when the slides 555 are actuated to set up the type segments, until the thick teeth thereon engage the cooperating tooth of the comb 551. Hence, when the slides 555 have actuated to dispose the proper type characters in printing position all of the pinions 532 are disposed in a zero position. In this respect it will be understood that if a pinion 532 is in zero position at the time the teeth of the comb 551 are moved into position to cooperate with these teeth, the associated tooth on the comb 551 will at once engage the thick tooth 550 to therefore, as stated above, hold such a pinion against rotation.

During the time the slides 555 are moving to set up the type segments which results in disposing all of the pinions 532 in zero position with one of the two thick teeth 550 thereon in engagement with the cooperating tooth on the comb 551, the pinions 532 are disengaged from the gear segments as 531 and, during the time the pinions 532 are being moved to zero position, the rockers 529 carrying the gear segments 531 are restored to zero position. It is the bail 510 that is effective to restore the rockers 529 to zero position and when this is to be effected, the cam 500, Fig. 35, acts on the roller 501 on the rocker 502 to thereupon move the links 508 and 509, Figs. 35 and 26, downwardly to thereby move the bail 510 downwardly against the effect of springs as 512. In so moving, the bail is effective on the toe portions 511 of the slides 483 to restore these slides to a zero position. Movement of the slides 483 into their zero position is effective, through the toe portions 521, on the pins 520 on the rockers 511 which, through the arms 516 thereof are effective, through the Bowden cables 515, to move the rockers 529 against the effect of the springs 548 to thereupon dispose the rockers 529 in zero position. A dwell on the cam 500 is effective to retain these parts so zeroized in zero position.

Moreover, the cam 498 also becomes effective on the roller 497, Fig. 26, so that through the lever 495 and link 494 the fingers 482 are retracted from the position in which they are effective to cooperate with the shoulders as 481. Hence, the actuating part of the setting up devices is in an at rest position when the rockers 529 are zeroized.

Thus, the pinions 532 are disposed in a zero position when the slides 555 have acted to dispose the proper type characters on the type segments in printing position and the rockers 529 are also disposed in zero position during the time this is effected, but at this time the pinions 532 are still meshed with the racks 554. Therefore, subsequently, in the operation of the machine, as will

be described, the cam plates 525 and 526 are actuated to move the teeth of the pinions 532 back into mesh with the teeth of the gear segments 531 and when the shaft 533 carrying these pinions is moved downwardly to bring this about, which is effected by counterclockwise movement, as viewed in Fig. 26, of the cam plates 525 and 526, the adjusting screw 553 moves away from the plate 538 which thereupon, under the influence of the spring 552, is effective to retract the teeth of the comb 551 from cooperating relation with the thick teeth 550 on the pinions 532. This comb is in this retracted position at the time the pinions 532 mesh with the gear segments 531.

In this respect it is to be noted that the pinions 532 also rotate counter-clockwise, as viewed in Fig. 26, both when they are being set up by actuation of the rockers 529 and when these pinions move to zero position to control the positioning of the slides 555. Furthermore, it has been explained hereinabove that at the time the rockers 529 are to be effective to set up the pinions 532 in digit representing positions, such pinions are to be disposed in initial positions representative of 9.

Consequently, after the teeth of the pinions 532 have been meshed, as aforesaid, with the teeth of the gear segments 531, because both the pinions 532 and the rockers 529 are at this time disposed in a zero position, it is necessary to so actuate the rockers 529 and the pinions 532 that the pinions will be disposed in a position representative of 9, as should be the rockers 529 and therefore the slides 483. Hence a drop 556, Fig. 35, on the cam 500 moves into cooperating relation with the roller 501 and is effective to so elevate the rod 510 that the slides 483 move in an amount equivalent to that in which they move to represent a single digit and in so doing the slides 483 move from the aforesaid zero position, into which they were moved, into an initial position representative of 9. Thereupon the springs 548 cause the rockers 529 to move into initial positions representative of 9 inasmuch as such movement of the rockers 529 will be permitted upon the just described movement of the slides 483 by reason of the interconnection between these devices afforded through the Bowden cables and associated devices. The roller 501 remains on the drop 556 on the cam 500 until, as explained hereinabove, the bail 510 is to be permitted to move upwardly to enable the slides 483 to move under the influence of springs as 512 to digit representing positions whereupon, as explained hereinabove, the rockers 529 and pinions 532 are moved to similar digit representing positions. It will therefore be seen that the slides 483, rockers 529 and pinions 532 are disposed in initial positions representative of 9, as has been referred to hereinabove, at the time the fingers as 482 are to be advanced or elevated through sensing movements to cooperate with positioned shoulders 481 to be effective to dispose the pinions 532 in digit representing positions corresponding to those into which summation members 375 move, as explained hereinabove.

Summarizing the manner in which the type segments TS are set up, it should first be recalled that when the pinions 532 are shifted downwardly from engagement with the racks 554, the pinions 532 are in zero positions, and are moved into engagement with gear segments 529 that are also in zero positions. Then, as a preliminary to the next sensing operation, the sensing numbers 483 are elevated from their zero positions through a distance representative of one unit, and this re-

sults in counter-clockwise movement of the pinions 532 from their zero positions to their initial or "9" positions. Having thus located the sensing members 483 and the pinions 532 in such initial positions, it becomes important to note the extent of the sensing movement that takes place for the various digits that may be represented by the shoulders 481 on the summation members 375, and in this connection it will be recalled that when the position of a shoulder 481 is representative of 9, the sensing member 483 will move upwardly for only the slight distance necessary to take up operative clearance. Furthermore, it will be recalled that where a shoulder 481 is so positioned as to be representative of zero, the sensing member 483 will move through an upward sensing stroke equal to nine units. As to intermediate digital values that may be positionally represented by the shoulders 481, a representation of the digit 8 will permit an upward sensing movement of one unit; a representation of the digit 7 will permit a sensing movement of two units, and so on, so that a representation of the digit 1 by a shoulder 481 results in a sensing movement of eight units for the associated sensing member 483.

Hence, when a representation of the digit 9 by a shoulder 481 is sensed by a sensing member 483, the related pinion 532 remains in its initial or 9 position; while sensing of any other digit represented by a shoulder 481 causes counter-clockwise movement of the related pinion 532 from its initial position to a position representative of the same digit that is represented by the sensed shoulder 481. Thus at the conclusion of the sensing operation the various pinions 532 are disposed in positions that are representative of the digits that are to be set up on the related type segments TS.

Prior to the time when the type segments TS are to be set up, the slides 555 and 555₁ are shifted to their zero positions by their related restoring bails, and the set up pinions 532 are then elevated into engagement with the racks 554. As this is done, the zero stop 538 is shifted to its active position. The slides 555 are then freed for their resiliently imparted movement to the left, Fig. 26, thereby to tend to impart counter-clockwise zeroizing movement to the pinions 532. Such zeroizing movement of a particular pinion 532 is terminated by engagement of a broad tooth 550 thereof with a tooth 551 of the zero stop 538, so that the extent of the zeroizing movement corresponds with the digit represented by the aforesaid set position of the pinion. Thus where a pinion 532 has been retained in its initial position wherein it represents 9, the zeroizing movement of such pinion will be equal to nine units, and the associated type segment TS will move from its zero position through nine spaces so as to set the 9 type face thereof in printing position; similarly, the representation of any other significant digit on a pinion 532 will cause the zeroizing movement to be equal to a corresponding member of units, thereby to set the corresponding type face in printing position; while a representation of zero on a pinion 532 serves to prevent counter-clockwise movement of such pinion, thereby to retain the related type segment TS in position to print zero.

As has been explained, at the time the pinions as 532 are retracted from engagement with the teeth of the gear segments as 531 they are moved into engagement with teeth of the racks as 554 on slides as 555. When this occurs the slides as 555 are disposed in positions representative of zero,

which is to say, these slides are so disposed that the type segments, described presently, respectively associated therewith are located in such positions that type characters thereon are positioned so that zeros would be printed therefrom if such type segments were not moved. The slides as 555 are freed to the effect of springs to dispose the proper type characters on type segments associated therewith in printing position under control of the main cam shaft 560 of the printing unit generally indicated by 600 which is mounted in the side frame members 504 and 505 forwardly of the multiplying mechanism M in the present instance. It is to be remembered, however, that since the arrangements including the rockers as 529 and the pinion as 532 are also supported between the side frame members 504 and 505 and since the rockers as 529 are connected to cooperating devices in the multiplying mechanism M through Bowden cables 515, as described hereinabove, the printing unit including the sets of type segments TS1 and TS2 and setup mechanisms such as that embodying the rockers 529 and associated mechanisms could be located at any desired position in the machine to enable impressions to be made from the type segments onto sheets as S or proof sheets as PS1 where and as required by the constructional characteristics of the machine in which such devices are embodied.

The aforesaid cam shaft 560 and the main cam shaft 499 of the multiplying mechanism M are driven from the main drive shaft 90 and to this end a pair of pulleys 561 and 562, Fig. 9, are fast on the drive shaft 90. An endless belt as 563, Figs. 9, 25 and 34, leads from the pulley 562 to a pulley 564 fast on a shaft 565, Figs. 9, 25 and 34, journaled in bearings in the side frame members 504 and 505. A gear 566, Figs. 9 and 34, is also fast on the shaft 565 and meshes with a gear 568 that is rotatably mounted on the main cam shaft 499 of the multiplying mechanism. A clutch of the character shown and described in my aforesaid copending application Serial No. 239,561, filed November 8, 1938, includes a collar 569 that is slidably but non-rotatably mounted on the cam shaft 499 and when the solenoid 570, Fig. 9, for this clutch is energized, this collar so moves the clutch teeth thereon as to engage clutch teeth on the hub of the gear 568. Thereupon the cam shaft 499 is sent through a single rotation to bring about a cycle of operation of the multiplying mechanism M.

Furthermore, an endless belt 571, Figs. 9, 25 and 36, is passed about the pulley 561, Fig. 9, and a pulley 572 fast on the jack shaft 573 journaled in bearings provided on the frame including the main side frame members 504 and 505. A pinion 574, Fig. 36, fast on the jack shaft 573 meshes with a gear 575 rotatably mounted on the main cam shaft 560 of the printing unit 600. A one-revolution clutch of the character shown and described in my aforesaid copending application Serial No. 239,561, filed November 8, 1938, includes a sleeve 576 that is slidably but nonrotatably mounted on the cam shaft 560. When the solenoid 577, Fig. 25, of this clutch is energized, clutch teeth on the sleeve 576 engage clutch teeth on the hub of the gear 575 and thereupon the main cam shaft 560 of the printing unit 600 is sent through a single revolution to effect an operation of this printing unit.

It will be understood that the clutches including the solenoids 570 and 577, Figs. 9 and 25, 75 which respectively control the operation of the

multiplying mechanism M and the printing unit 600, are operated in timed relation with each other, this being explained more fully hereinafter with reference to the operation of the machine. However, it is necessary that the cam shaft 560 of the printing unit 600 not be set in operation until after the multiplying mechanism M has so operated that the setting of the pinions as 532, Fig. 26, in digital positions will have been effected and such pinions will have been engaged with the racks as 554 on the slides as 555 for when the cam shaft 560 is set in operation the slides as 555 will be caused to move through a setting up operation.

While the setting up devices, including the rockers 529, are, in the present instance, associated with the slides 555 at a position in the extent thereof located near the type segments as TS1, it will be understood that, if desired, these setting up devices could be associated with slides 555 near the type segments as TS2. Moreover, each slide as 555 comprises two sections as 555r and 555f, the sections as 555r in the present instance being associated with the type segments TS1 and the slides 555f being associated with the type segments TS2. In this instance the slide sections 555r and 555f are mounted in combs as 551a, Figs. 26 and 27, extended between and carried by the side frame members 504 and 505, and in order to insure free movement of the slides in these combs each slide section has a pair of slots as 552a formed therein in each of which slots a roller as 553a is disposed, these rollers being carried by rods as 554a extended between and carried by the side frame members 504 and 505, and it is these rollers that insure free movement of the slide sections 555r and 555f.

Furthermore, by dividing the slides as 555 into two sections as aforesaid, I am enabled to simultaneously set up type segments in sets thereof as TS1 and TS2, but by separating the sections of the slides as 555 I can, after the setup of such type segments, retain one set of type segments in setup condition and return the other set of type segments to their normal at rest positions, this being advantageous and necessary in certain operations, as is described more fully hereinafter.

However, since it is advantageous to simultaneously set up all type segments that are to be set up, I so arrange the sections as 555r and 555f of the slides as 555 that may be moved conjointly, and to this end pawls as 578 are pivotally mounted on the sections 555r, as indicated at 579, and these pawls include toe portions as 580, Figs. 26 and 27, that are urged into recesses as 581 in the sections 555f. To this end rollers as 582 on a rod 583, Figs. 25 and 27, are respectively disposed above the pawls as 578 and the rod 583 is mounted in arms as 584, Fig. 25, pivotally mounted on the side frame members 504 and 505, a spring as 585a acting on these arms and therefore the rod 583 and rollers 582 to urge the toe portions 580 toward the recesses 581. At a predetermined time in the course of operation of the printing unit 600 and, in a manner described hereinafter, the toe portions 580 are retracted from the recesses as 581 to thereby disconnect the sections 555r from the sections 555f to permit the type segments associated with one or the other of these sections to be retained in setup position and to permit the type sections associated with the other sections to be restored. In the present instance the type segments TS1 are retained in setup position while the type segments TS2 are restored.

In the present instance, at the time the pinions 75

as 532, Fig. 26, are moved into engagement with the racks as 554, the toe portions 580 are seated in the recesses 581 so that the sections 555r and 555f may move as a unit. When these sections are interconnected to move as a unit they are retained in a position to represent the digit 0 by a bail 585, Fig. 27, that extends between arms as 586, Fig. 27, pivotally mounted on a shaft 587 extended between and carried by the side frame members 504 and 505. The bail 585 is disposed in recesses in the upper edges of the slide sections 555f which define shoulders as 588, Fig. 27, against which the bail bears to retain the slides 555 in their respective zero representing positions. Moreover, shortly after the cam shaft 560 is set in operation, a roller 589 on an arm 591 depending from one of the arms 586 passes from a dwell on the cam 590, Figs. 27 and 36, on the cam shaft 560 and thereby causes the bail 585 to move to the left, as viewed in Fig. 27, to thereupon free the slides 555 to the effect of springs as 592 and 593. The springs as 592 extend between spring anchors as 594 on each slide 555 and rods as 595 extend between ears as 596 on the side frame members 504 and 505. Similarly, the springs 593 extend between spring anchors as 597 on the sections 555r and rods as 598 extend between ears as 599 on the side frame members 504 and 505. Therefore, when the bail 585 moves to the left, as viewed in Fig. 27, the springs 592 and 593 are effective to move the sections 555r and 555f (which are interconnected at this time) to the left, as viewed in Figs. 26 and 27, to thereby bring about setup of the type segments as TS1 and TS2 which are connected to the aforesaid sections for movement therewith.

To this end a rack as 601, Fig. 26, is formed on the upper edge of each slide sections 555r and meshes with a gear segment as 602 provided on a rocker as 603 which is a part of each type segment TS1 that is adapted for cooperation with a slide section 555r. The rockers 603 are mounted for rotation about a shaft 604 that extends between and is carried by the side frame members 504 and 505. Another rocker as 605 is pivotally mounted on the shaft 604 in association with each rocker 603 and a segmental type bearing head 606 is provided on each rocker 605. Each such type bearing head bears, at the right-hand end thereof as viewed in Fig. 26, a type character from which a star or other blanking character can be printed and to the left, as viewed in Fig. 26, type characters for respectively printing the digits 0 to 9 are provided on the segments 606. Springs as 607 extend between the rockers 603 and 605 and urge a stop as 608 on each rocker 605 into engagement with a shoulder afforded on each rocker as 603 and the spring 607. The engagement of the stops 608 with shoulders 609 is effective to cause the rockers 605 and 603 to move conjointly clockwise, as viewed to Fig. 26, this arrangement, however, enabling each rocker 605 to be pivoted counterclockwise, as viewed in Fig. 26, relative to its associated rocker 603 to thereby bring the aforesaid star printing type character into printing position in a manner and for a purpose to be explained presently.

The interengagement between gear segments as 602 with racks as 601 is such that normally the type characters on the segments 606 from which zeros may be printed are disposed in printing position. Therefore the type segments as TS1 are disposed in zero position when the slides as 555 are disposed in zero position. How-

ever, after the pinions as 532, Fig. 26, have been meshed with the racks as 554 and the cam shaft 560, Fig. 27, is set in operation, and the bail 585 starts to move to the left, as viewed in Fig. 27, the springs 592 and 593 are thereupon effective to move the slides 555 to the left, as viewed in Fig. 26. Such movement continues until a wide tooth 550 on the associated pinion 532 engages the co-operating tooth on the comb 551, there being no movement when, as explained above, the wide tooth 550 is already engaged with such a comb tooth for under such circumstances the type character for printing zero is already in printing position and is to remain there. In other instances, however, the slides 555, and therefore the rockers as 605, move in an amount sufficient to bring the proper type character into printing position, such type character being selected in accordance with the digital value to which the pinion 532 has been set to represent in the manner hereinabove explained.

In an instance such as the present one where the type characters TC on the segments 602 are to print the amount for which a check is to be payable, it is customary to print blanking characters above or to the left of the highest significant digit in the amount for which the check is to be payable. In this respect, in the present machine, Bowden cables as 515 are associated with but seven of the summation members as 375 for the reason that but seven type segments as TS1 are provided for printing the variable data VI because this enables amounts up to \$99,999.99 to be printed on the checks. This has been found in practice to be a greater amount than any that need be printed in the course of preparation of dividend checks. Furthermore, as is customary in the practice of preparing checks, where the two most right-hand columns pertain to cents, a zero is printed whenever this digit appears in either the units or the tens order of a cents amount. However, since some dividend checks may be prepared to provide for a payment only in cents and since it is customary to print blanking characters above the highest significant digit for which a check is to be payable, I have associated with each type segment as TS1, from which digits appearing in orders pertaining to dollars may be printed, an arrangement for moving such a type segment counterclockwise, as viewed in Fig. 26, when a blanking character should be printed in any order pertaining to dollars, such an arrangement not being provided in association with those type segments TS1 from which digits to appear in either order of cents may be printed.

Therefore, each rocker 605 of a type segment TS1 from which digits pertaining to dollars may be printed has a shoulder as 610, Fig. 26, provided thereon in position to cooperate with a pawl as 611, there being such a pawl for each shoulder 610. The pawls 611 are mounted on a shaft 612 carried by a rocker 614, Figs. 25, 26 and 27A, that has the side arms thereof disposed outwardly of and in juxtaposition to side frame members 504 and 505 to which these arms, and therefore the rocker 614 are pivotally connected as indicated at 615. A bar 616 extends between the side arms of the rocker 614 and has a plurality of leaf springs 616 mounted thereon in position to respectively bear on the pawls 611. Pivotal movement of the pawls 611 about the shaft 612 under the influence of the spring 616 is normally resisted by a bail 617 carried by a bracket 613 mounted for pivotal movement on the

shaft 612 as best shown in Fig. 26. A roller 617' on the bail 617 cooperates with a cam surface on the cam plate 614', Fig. 25, carried by the side frame member 505. In the manner explained hereinafter the rocker 614 is pivoted clockwise, as viewed in Fig. 26, and thereupon the bail 617 is moved from restraining position to enable the nose on each pawl 611 to cooperate with the associated shoulder 610, if said shoulder has not been advanced out of cooperating relation with this nose, in the manner explained presently. When a pawl 611 engages a shoulder 610 further rocking movement imparted to the rocker 614 is effective to shift the rocker 605 carrying such an engaged shoulder counterclockwise as viewed in Fig. 26. Such operation is enabled by the configuration of the cam plate 614' and is a result of the rocking of the rocker 614. It will be understood that such movement is imparted to the rocker 614 at a time in the course of an operation subsequent to that at which the type segments TS1 are set in digit representing positions.

In this respect, in an operation in which a type segment as TS1 is moved into such position as to dispose in printing position a type character TC thereon from which a significant digit may be printed, the associated pawl 611 is prevented from moving such a type segment counterclockwise. To this end an arcuate surface 618, Fig. 26, is formed on each rocker 605 beyond the shoulder 610 and in such position that when a type segment, and therefore the rocker 605 thereof, is moved into the just described position and the bail 617 is moved from restraining position, the nose of the associated pawl 611 will seat on this arcuate surface. It is this that is effective to prevent a rocker 605 being moved counterclockwise, as viewed in Fig. 26, and which enables whatever type character for printing a significant digit is disposed in printing position to remain there. Thus, only when a type segment is disposed in such position that zero may be printed therefrom is a pawl 611 effective to move this type segment in such a manner that a blanking character may be printed from the type segment and this occurs unless, as will be explained presently, the associated pawl is rendered ineffective to bring about such movement when the bail 617 is moved from restraining position as aforesaid.

In order that a pawl 611 may be rendered ineffective, for a purpose explained presently, each pawl bears a lug as 619 which extends in front of the pawl pertaining to the next lowest order. Therefore when a pawl 611 engages an associated arcuate surface 618 on one of the type segments TS1, the noses on all pawls 611 pertaining to lower orders are held from moving into engagement with the shoulders as 609 operatively associated therewith. This is effected because, in such an instance, a digit, not a blanking character, is to be printed in the lower orders. An example of this is where the amount of 608.17 is to be printed, in which instance the pawl 611 for the hundreds order will engage an arcuate surface as 618 and render the pawls for the hundreds and tens orders ineffective because if, in such a circumstance, the pawl for the tens order was not rendered ineffective it would bring a blanking character into printing position rather than the zero which is desired. Therefore, blanking characters are printed only in those orders above the highest in which a significant digit appears.

As best shown in Fig. 25, a latch 622 is pivotally

mounted, as indicated at 623, on the outer face of the side frame member 505. A spring 624 is effective to urge the free end of this latch toward a shoulder 625 on the adjacent arm of the rocker 614. When the rocker 614 is pivoted by means to be described presently to bring the plate 621 into engagement with the teeth 620, and to operate the pawls 611, as aforesaid, the latch 622 engages the shoulder 625 and under the influence of the spring 624 is effective to retain the plate 621 in engagement with the teeth 620 to thereby maintain and latch the type segments TS1 in their setup positions. This arrangement is utilized to retain the type segments TS in setup condition and until release thereof is to be effective at time explained hereinafter. However, in a manner to be described, the latch 622 is released from the shoulder 625 to enable the spring 626, Fig. 25, to restore the rocker 614 and thereupon withdraw the plate 621 from the teeth 620 to permit the type segments TS1 and the slide sections 555r to be restored to their normal at rest or zero positions.

When the type segments TS1 are latched by the latch 622 in setup condition to retain the type characters TC thereon in printing position, these type characters are disposed beneath an inked ribbon (not shown). In the present instance these type characters are located to be disposed beneath the printing face 281 on the main platen MP so that when, in the manner described hereinabove, this printing face is moved downwardly to printing position, an impression will be made on a portion of the check as S that is disposed between the aforesaid inked ribbon and the aforesaid printing face, the manner in which this portion of the check is disposed in such printing position being explained hereinabove.

It is desirable that the numerals in the amounts printed from the type characters TC on the check as S, be accurately aligned. To this end, a series of teeth 620 are formed on each rocker 603 in positions accurately related to the positions of the type characters TC on the type segment TS1 of which such rocker is a part and the teeth of each series are accurately related to the teeth in each other series. Hence by engaging an aligning means with the teeth 620, after the type characters TC have been disposed in printing position, I insure that neat impressions will be made from these type characters.

Therefore, I mount a bracket 622 on a shaft 623 carried by the rocker 614 and a knife edge plate 621 is provided on this bracket which is adapted to seat in those teeth 620 that are related to the type characters disposed in printing position. Leaf springs 622' carried by a bar 621' on the rocker 614 urge the plate 621 toward the teeth 620. The effect of these springs is resisted by a cam surface on the cam plates 614' that is engaged by a roller 623', Fig. 25, that is carried by the bracket 622. When the rocker 614 is rocked, in the manner described hereinafter, the knife edge plate 621 is engaged with the teeth 620 related to the type characters TC in printing position subsequent to the time the pawls 611 engage the shoulders 610 that are to be engaged thereby so that by the time the proper type characters TC are moved to printing position, the plate 621 will engage the teeth 620 related to such type characters and thereupon these type characters will be so aligned that a neat impression may be made therefrom. The configuration of the cam plate 614' is such as to so control the position of the roller 623' that the desired move-

ment of the bracket 622 and plate 621 is effected in the course of the rocking of the rocker 614 which moves the roller 623' relative to the cam plate 614'.

As has been explained hereinabove, at the time the type segments TS are set up, the slide sections 555r and 555f are interconnected by reason of the fact that the toe portions 580 on the pawls 578, Fig. 26, are seated in the recesses 581. Therefore at the time the type segments TS1 are set up, the type segments TS2 are simultaneously set up. Inasmuch as the type segments TS2 and the parts associated therewith are in most respects, similar to the type segments TS1 and the parts associated, those parts in and associated with the type segments TS2 which correspond to those hereinabove described with reference to the type segments TS1 are designated by a similar reference character, except that the suffix "f" is added to such reference characters where they are applied to the type segments TS2 and associated parts. However, in the present instance where the type segments TS2 are employed for producing impressions of variable data as V1 and V2 on proof sheets as PS1, it is not necessary to print blanking characters or stars above the highest order in which a significant digit appears. Therefore pawls as 611 are not associated with the type characters TS2 to enable these type segments to be moved into a position from which blanking characters might be printed.

Furthermore, the type TCf on the type segments TS2 are mounted on a segment 630 rather than on a segment or rocker 605 that is included in the type segments TS1. The segment 630 is pivotally mounted, as indicated at 631, on an arm 632 of a rocker 633 that is mounted on the shaft 604f and which includes an arm 634 that is secured, as indicated at 635, to the segment 603f. Moreover, a bracket as 636 is provided on each arm 632 and springs as 637 extend between this bracket and the segment 630, and these springs are effective to dispose the segment 630 in position to arrange the type characters TCf in printing position in association with an inked ribbon (not shown).

Moreover, in the instance of the type segments TS2, hammers as 638 are associated with each type bearing segment 630 to drive the type characters TCf thereon toward the aforesaid inked ribbon, whereby an impression is made on the web W which is later divided into proof sheets PS1, as explained hereinabove. In such a printing operation the printing face 302, Fig. 24, of the proofer platen PP serves as a backup member to insure that a neat impression will be made when a hammer as 638 forcibly drives a type bearing segment as 630 toward the inked ribbon. Furthermore, in this instance, instead of printing blanking characters above the highest significant digit appearing in an amount to be printed from setup type characters as TCf, the arrangement is such that those hammers as 638 associated with type bearing segments 630 above the highest order in which a significant digit is to be printed remain ineffective and are not forced toward a type bearing segment 630. Hence, no impression whatsoever is made on the web W above the highest significant digit that is printed thereon in a printing operation from the type segments TS2. Moreover, the printing face 302 of the platen PP is ineffective to make an impression on the web W since this face merely serves as a backup member and the hammers 638

must be operated to enable an impression to be made from the type characters TC_f .

Consequently, only those hammers 638 which are to be effective in a printing operation are rendered effective and in this respect the hammers 638 are normally latched in ineffective position. In this respect it will be noted that each hammer as 638 is mounted on a rocker as 639, Fig. 27, and each such rocker includes a lug 640. These lugs 640 are mounted for pivotal movement about a rod 641 extended between and carried by the side frame members 504 and 505. An arm as 642 extends from each lug as 640 and a spring 643 is effective on each such arm to normally urge the hammer as 638 forcibly toward the type bearing segment as 630. Hence, when the rocker 639 bearing a particular hammer 638 is unlatched, the hammer will strike a forceful blow to insure that a neat impression will be made from the setup type character TC_f .

Each rocker as 639 also includes an arm 644 that normally engages a shoulder 645 on a latch as 646, the latch as 646 being pivotally mounted on a rod 647 that extends between and is carried by the side frame members 504 and 505. Each latch 646 includes a nose 647 that is disposed in alignment with a shoulder 648 provided on each segment as 603f. Then, whenever a type segment TS2 is moved into a position to dispose a type character TC_f thereon from which a significant digit may be printed in printing position, the shoulder 648 engages the nose 647 and so pivots the latch that the shoulder 645 is moved from engagement with the arm 644 of the associated rocker 639 to thereby free the rocker 639 and therefore the hammer 638 to the effect of the springs 643. This, however, occurs during the time when the type segments as TS2 are being set up and therefore a latch, to be described presently, is afforded for restraining the rockers as 639 against movement under the influence of springs as 643 until the time in the operation of the machine at which an impression is to be made from type characters as TC_f .

Moreover, when an amount as 608.17 is to be printed, the type segments from which the zero in such an amount should be printed will not be moved from its zero position yet in such an instance an impression should be made from the type character TC_f thereon from which zero may be printed. Therefore lugs as 649 are provided on each latch as 646 and the lug on each such latch extends over the latch pertaining to the next lowest order. Hence, when the type segment TS2 from which the highest significant digit in any amount is to be printed moves from zero position, the lugs as 649 are effective to so condition the latches as 646 on the type segments from which lower digits in the amount are to be printed that when the hammers 638 should be operated this may be brought about. Thus, in the instance where an amount as 608.17 is to be printed, the type segment TS2 for the hundreds order of dollars moves from zero position and thereupon the lug as 649 thereon conditions the latch 646 for the type segment TS2 pertaining to the tens order of dollars so that the hammer 638 for this type segment may be operated to print the zero in the amount 608.17.

In order that the hammers as 638 will not strike the type bearing segments as 630 until an impression is to be made from the type characters as TC_f , a lug as 650 is provided on each rocker 639 and a bail is normally disposed to engage these lugs to thereby restrain the hammers 638 against

the effect of springs as 643. The bail 651 is carried by a pair of arms as 652 fast on a shaft as 653 journaled in suitable bearings carried by the side frame members 504 and 505. A spring 5 654 is normally effective on one of these arms to urge the bail 651 toward the lugs 650. A link 655 has one end thereof fast to the shaft 653 and another link 656 is fast to the opposite end of the link 655. The link 656 is, in turn, pivotally connected to the free end of a lever 657 which is pivotally mounted on and carried by a stud 658, Figs. 27 and 36, carried by the side frame member 505. A roller 659 on the lever 657 is held in engagement with the periphery of a cam 10 660 by the aforesaid spring 654.

At the time in the operation of the printing unit 600 when impressions are to be made from the type characters TC_f , the lever 657 is so actuated by the cam 660 that the bail 651 is retracted from the lugs 650 and then the hammers are forced by springs 643 toward the type bearing segments 630 whereupon impressions are made from the type characters TC_f onto the web W.

Leaf springs as 661 urge the latches as 646 into 25 their latching positions and when the bail 662 is operated in the manner described presently to restore the rockers 639 to their latched position these leaf springs, which are carried by a bar 663 that is extended between and carried by the side frame members 504 and 505, dispose the 30 latches 646 in their latched position and retain them in these latches, are released in the manner hereinabove described. The bail 662 is carried by an arm 663 that is pivotally mounted on a stud shaft 664 carried by the side frame member 504. A pair of arms 666 is connected to the arm 663 and has a roller 665 at the free end thereof that rides on the periphery of a cam 667 fast on the cam shaft 560. This cam is effective in 35 the course of operation of the printing unit 600, after the hammers 638 have been released to effect a printing operation, to cause the arm 663 to pivot and thereupon the bail 651 is moved upwardly into engagement with the rockers 639 to so pivot these rockers about the rod 641 that the latches 646 may be effective thereon to latch these rockers in their normal at rest position.

It has been explained hereinabove that the rocker 614 and, therefore, the rocker 614f, Figs. 50 25 and 27A, are to be rocked so as to engage the plates as 621 and 621f with the teeth as 620 and 620f to thereby align the type segments as TS1 and TS2 and also to latch the type segments TS1 in setup position. To this end a cam 670, 55 Figs. 27 and 36, is provided on the cam shaft 560 and a roller 671 is engageable with the periphery thereof, this roller being carried by a lever 672 pivotally mounted on a stud shaft 673 carried by the side frame member 505. A link 60 674 has the lower end thereof pivotally connected to the lever 672 and the other end thereof is pivotally connected, as indicated at 675, to an arm 676, Fig. 27, on the rocker 614f, adjacent the side frame member 505. Furthermore since 65 the rockers 614f and 614 are to move conjointly in the course of the rocking movement thereof to actuate the plates 621 and 621f, as aforesaid, a link 678, Fig. 27A, is pivotally connected to the rocker 614f, as indicated at 678'. Moreover, a 70 pin 680' is provided on the rocker 614 and this pin is disposed in a slot 680 in the link 678.

Therefore when a rise on the cam 670, Fig. 27, acts on the roller 671 to pivot the lever 672 downwardly, the link 674 is moved downwardly and 75 this is effective through the arm 676 to pivot

the rockers 614 and 614f so as to move plates 621f and 621 into engagement with the positioned teeth 620f and 620 for the purpose explained above. In such pivotal movement of the rocker 614f, the left-hand end of the slot 680, as viewed in Fig. 27A, is engaged with the pin 680' and it is this that assures the desired conjoint movement of the rocker 614f and 614.

Shortly after an impression has been made from the type characters TCf, the cam 670 is effective to cause the rocker 614f to be restored to its at rest position wherein the plate 621f is disengaged from the teeth 620f and therefore the type segments TS2 may be restored to their zero position. However, at this time the latch 622, Fig. 25, is effective to latch the type segments TS1 in their setup condition, as has been explained. Hence when the rocker 614f restores to its at rest position and thereupon moves the link 670 to the left, as viewed in Fig. 27A, the slot 680 enables this movement to be effected without causing movement to be imparted to the rocker 614.

After the time the link 674 pivots downwardly to rock the rockers 614f and 614, the slide sections 555f and 555r are to be disconnected one from the other to enable the type segments TS2 to restore to their zero positions while the type segments as TS1 are still latched in their setup positions. Hence, a link 681, Fig. 25, is connected to the rocker 614 and this link extends to a rocker 682 pivotally mounted, as indicated at 683, on a plate 684 carried by the side frame member 505. The rocker 682 has a cam slot 685 therein in which a roller 686 is disposed, this roller being rotatably mounted on the end of a bail 687, Figs. 25 and 27, that extends beneath the pawls 578 that are pivotally mounted on the slide sections 555r, as explained hereinabove. The bail 687 is carried by a pair of arms 688 and 689, Figs. 25 and 27, that are respectively pivotally mounted on the side frame members 504 and 505, as indicated at 690 and 691. In this respect it is to be noted that a bar 692, Figs. 25 and 27, extends between upstanding lugs on the arms 688 and 689 and carries a comb spring, generally indicated by 693, the teeth of which are respectively effective on the pawls 578 to urge the pawls toward the bail 687 and the toe portions 580 toward the recesses 581 in the slide sections 555f.

The configuration of the cam slot 685 is such that upon movement of the rocker 614 to effect latching of the type segments TS1, as aforesaid, this cam slot will be effective on the roller 686, after the plate 621 has engaged the teeth 620 and the latch 622 has latched the rocker 614, to raise the bail 687, Fig. 27. This bail thereupon engages the under sides of the pawls 578, whereupon against the effect of the comb spring 693 these pawls are pivoted upwardly to retract the toe portions 580 from the recesses 581. Thereupon the slide sections 555f are disconnected from the slide sections 555r. It is to be noted, however, that since the slide sections 555f are connected through the rack 601 and the gear segments 602 with the type segments TS1 and that these type segments will remain in setup position by reason of the latching effect of the latch 622, Fig. 25. Hence, the slides 555f do not restore to normal zero position when the link 674, Fig. 27, moves upwardly to effect restoration of the rocker 614f. However, since such upward movement of the link 674 does effect restoration of the rocker 614f, the type segments TS1 and the

slides 555f may restore to their normal zero positions and this is done upon restoration of the rocker 614f to its at rest position. It is to be noted, however, that the link 681 is connected to the rocker 614 and therefore the rocker 682 remains in such position that the cam slot 685 therein is effective to maintain the bail 687 in such position as to keep the toe portions 580 on the pawls 578 in their retracted position to thereby prevent these toe portions from re-seating in the recesses 581 and interconnecting the slide sections 555f with the slide sections 555r.

In the present machine the type segments TS1 are still in their setup position at the end of a cycle of operation but the latch 622 is released to enable restoration thereof very shortly after the initiation of a cycle of operation in which the type segments TS1 are to again be set up. Inasmuch as the type segments TS1 are not to be set up unless the multiplying mechanism M is set in operation I effect release of the latch 622 and restoration of the type segments TS1 and therefore the slide sections 555r under control of devices included in the multiplying mechanism.

Therefore a cam 460a, Fig. 26, is provided on the cam shaft 499 of the multiplying mechanism M. A roller 461a mounted on an arm 462a engages the periphery of the cam 460a and shortly after the multiplying mechanism M is set in operation this cam causes the arm 462a to be moved to the left, as viewed in Fig. 26. The arm 462a is fast to a shaft 463a journaled in bearings provided on the side frame members 504 and 505 and when the arm 462a is moved, as just described, the arms 464a fast thereon are effected to move the bail 465a carried thereby toward the rear ends of the slide sections 555r so as to thereby restore the slide sections and therefore the type segments TS1 to their zero positions.

Very shortly after the arms 464a so move an adjustment screw 466a carried by a bracket 467a on an arm 464a engages a pin 468a, Fig. 25, on the latch 622 and pivots this latch against the effect of the spring 624 in such direction as to disengage this latch from the shoulder 625 on the arm of the rocker 614 it engages to latch the rocker 614 in its latched position. This frees the rocker 614 to the effect of the spring 626, Fig. 25, and thereupon the rocker 614 restores to its normal at rest position so to thereby retract the plate 621 from the teeth 620 and therefore enable the bail 465a to restore the slide section 555r and type segments TS1.

Moreover in the course of such restoration of the rocker 614 the link 681 so pivots the rocker 682 that the cam slot 685 therein is effective to cause the bail 687 to be moved to its retracted position and thereupon the teeth of the comb spring 693 urge the pawls 578 downwardly so that when the slide sections 555r are restored to their normal at rest positions, at which time the slide sections 555f will be at their at rest positions, the toe portions 580 may enter the recesses 581 and thereby interconnect the slide sections 555r and 555f for conjoint movement.

It will be seen therefore that the slide sections 555f are connected to the slide sections 555r only when the type segments TS1 and TS2 are to be set up and that at all other times the sections 555f may move independently of the sections 555r. It is this that enables the sections 555f to be utilized to set up the type segments TS2 when totals are to be printed on the web W, as will be explained. Furthermore, the amounts which are accumulated to afford such totals are entered

into the accumulator AC-PT in those instances where variable data V1 and V2 are printed upon restoration of the slide sections 555f to their normal at rest zero position. It will therefore be seen that it is important to maintain the slide sections 555f disconnected from the slide sections 555r but this is effectively accomplished by the latch 622, Fig. 25, in the manner hereinabove explained.

VARIABLE FACTOR PRINTING

It has been explained hereinabove that in the present machine the variable data as V2 is printed on the checks as S and the proof sheets as PS1. In the present instance, these data are the numerical amount represented on each printing and control device as D that has coded perforations as 85 therein and this, in the case of preparation of dividend checks, is the number of shares of stock owned by the particularly person or the like to whom the printing and control device pertains. While a separate mechanism could be provided for setting up the type segments in the groups thereof as TS1 and TS2 that are employed to print the variable data as V2, I have found it advantageous to incorporate into the multiplying mechanism M an additional plate somewhat similar to the plates as 358, Figs. 28 and 29, included in the multiplying mechanism and I have so arranged this special plate, which is indicated generally by 770 in Fig. 38, as to enable type segments to be set up directly under control of the sensing means included therein for so to do enables me to set up type segments to represent the digit that appears in each digital order represented by coded perforations as 85 on the printing and control devices as D.

In order to enable this to be accomplished through the use of a plate as 770 included in the multiplying mechanism M, a special templet as SPT, Figs. 37 and 38, is included in each templet-gang TG and, as best shown in Fig. 38, this templet has a series of steps as SPTS formed thereon which, leading from right to left as the templets SPT are viewed in Fig. 38, respectively represent the digits 0 to 9. These steps SPTS are so related to the steps PS on the positioning templet PT of the templet gang TG in which a particular templet SPT is included that when, for example, in the manner described in full detail in my aforesaid copending application Serial No. 313,146, a step PS representative of the digit 3 is determinative of the positioning of the associated templet-gang TG, a step SPTS representative of the digit 3 is aligned with the sensing means adapted for cooperation therewith carried by the plate 770. Hence, upon engagement of this sensing means with such a positioned step SPTS, the particular sensing member will assume a digit representing position corresponding to the digital value of the particular step SPTS which, in the aforesaid instance, would be representative of the digit 3.

It will be understood that, like the templet-gange TG in which they are included, the templets SPT respectively pertain to the units, tens, hundreds, and so on orders of the variable factor, the multiplier in this instance, which is represented by the coded perforations 85 in the printing and control devices D. Therefore, sensing fingers as 771-U, 771-T, 771-H, 771-TH and 771-TT, Fig. 38, are provided on the plate 770 for cooperation with the positioning templets SPT included in the templet gangs TG that respectively relate to the units, tens, hundreds, and so on orders. Hence, when the sensing finger 771-U

cooperates with a step SPTS on the templet SPT included in the templet-gang TG-U, this sensing member assumes a position representative of the digital value represented by coded perforations as 85 in the printing and control device D in the units order, and this applies with respect to each sensing finger 771 in so far as the particular order in which it pertains may be concerned.

In this instance the sensing fingers 771 are each to represent a digital value but the values sensed thereby are not accumulated in a summation member as 375 in this instance, for readings are taken directly from the positions into which the sensing fingers 771 move, as will be explained presently. Nevertheless I provide a summation member 375s on the plate 770 which is acted on by a spring as 376, Fig. 25, just as are the summation members 375. Furthermore, a rectilinearly moving planetary gear train including pinions as 364s and rack slides as 365s and 366s, the various sensing fingers 771 are connected to the summation member 375s. Therefore, when this summation member 375s is moved downwardly along with the other summation members 375, the sensing fingers 771 are moved upwardly and into cooperating relation with the steps SPTS operatively aligned therewith, these steps being operatively aligned with the sensing fingers 771 upon the disposing of the templet-gang TG embodying the templet SPT on which such steps are provided in a digit representing position, this being described, as referred to hereinabove, in full detail in my aforesaid copending application Serial No. 313,146.

Each summation member 375s has a pinion 771' fast thereon which meshes with a rack on a slide 772' having slots 773' therein, in which flanged rollers 774' carried by the plate 770 are disposed, this arrangement affording a support for the slides 772'. The pinions 771' also mesh with a rack on a rack slide 365a. Therefore, when a summation member 375s moves into a digit representing position, the slide 772' connected thereto is also moved into a corresponding digit representing position, and it is such position of the slide 772' that is utilized to effect setup of type segments as TS1 and TS2 to enable the variable data V2 to be printed therefrom.

Each slide 772' is connected through a Bowden cable 515s, Fig. 38, to a slide as 522, Fig. 26, which like other of the slides 522 is operative to set up the type segments from which the variable data are printed, as explained hereinabove. Those slides 522 to which the Bowden cables 515s are connected are, through the intermediary of devices hereinabove described, operative to dispose pinions 532 in digit representing positions to be effective to dispose slides 555 in digit representing positions and this, in turn, is effective to dispose type segments TS1 and TS2 in position to enable variable data V2 to be printed therefrom.

In this respect it is to be recalled that when the slides as 555 are moved to digit representing positions, the thick teeth as 550 on the pinions 532 are moved from their digit representing position back to a zero position and into engagement with teeth included on the comb 551. It has also been described hereinabove that in the final restoration of the devices associated with the slide 522 set up from the multiplying mechanism M the related pinions 532 are moved into a position representative of 9 to be ready to receive the next entry.

However, those pinions 532 which are operative

to set up the slides 555 which function to set up type segments as TS1 and TS2, in the manner hereinabove described, from which variable data V2 may be printed are not restored from a zero position wherein they engage the teeth of the comb 551 but are permitted to remain in such zero position when the other pinions 532 are restored from such zero position to a position to represent 9 as is done in the manner explained above under control of the multiplying mechanism M. Hence, if the Bowden cables as 515s are to function to set up pinions as 532 controlling type segments from which the variable data V2 may be printed, in a manner like that in which the Bowden cables 515 effect this, it is essential that the associated pinions as 532 be capable of being moved in a setting up operation in an amount equal to that through which these pinions move from one digit representing station to another before they begin to actually enter a represented digit in the associated pinion 532.

In this respect it is to be noted that the steps as SPTS, Fig. 38, representative of 9 on the templets SPT, indicated by SPTS-9, are those which will be disposed closest to the cooperating ends of the sensing fingers as 771 when the templet-gangs TG are set in digit representing positions. If the sensing fingers 771 were to cooperate with the steps as SPTS in the same manner as that in which the sensing members as 359, Fig. 29, co-operate with steps as PTS, the sensing fingers 771 would only move to take up operative clearance when steps as SPTS-9 were operatively associated therewith and therefore the associated pinions as 532 would remain in zero position. Consequently, when the sensing fingers as 771 are in their at rest positions they are disposed in a retracted position, the amount of such retraction being equivalent to the amount such fingers move to represent one digit. Hence, if a step SPTS-9 is operatively associated with a sensing finger 771, such sensing finger moves, prior to engaging such step, an amount sufficient to move the associated pinion 532 from its normal at rest zero position into a position representative of 9. Therefore, when the associated Bowden cable thereafter attains its proper digit representing position, determined by the positioned step SPTS, the associated pinion 532 is in proper digit representing position. Hence, when such pinion functions to set up the associated slide 555, this slide and therefore the associated type segments TS1 and TS2 act to dispose the proper type character as TC in printing position.

Furthermore, when the sensing fingers 771 co-operate with a zero representing step SPTS-0, the sensing fingers, in effect, move through an amount equivalent to which they would move to represent 11. In so doing, the associated pinion 532 is moved from the normal at rest zero position into a zero representing position so that, as explained hereinabove, when this pinion 532 is meshed with the cooperating rack on the associated slide 555, this slide 555 will not move. The reason for this is that rotation of the pinion 532 under control of the sensing finger 771 that co-operates with a step SPTS-0 will dispose a thick tooth 550 in position to at once engage a tooth on the comb 551. This pinion is, therefore, in its normal stopping position and consequently is effective to retain the type character TC, from which zero may be printed, in printing position.

Once the slides 555 controlling the printing of the variable data V2 have been set up, the sensing fingers as 771 may be restored to their aforesaid

normal at rest positions. In the present instance this is effected simultaneously with the restoration of sensing fingers as 359, Fig. 29, upon return of the summation members as 375 and 375s to their normal at rest position in the course of a cycle of operation of the multiplying mechanism M. However, at the time this restoration is effected, the pinions as 532, that are operatively associated with the sensing fingers 771, are not meshed with their associated gear segments 531 and therefore these pinions 532 will remain, as explained hereinabove, in a zero representing position.

OPERATION CONTROLLING MECHANISMS

It will be manifest from the foregoing description that the various operative mechanisms in the machine such as those for advancing the printing and control devices through the machine, the pumps as 259 and 260 which operate the platens MP and PP and other similar devices must operate in definite timed relation one with the other. Furthermore, as will be described more fully hereinafter, there are times at which it will be advantageous to control the operation of one such mechanism from the means operating another such mechanism as, for example, there will be times when it will be advantageous to operate one or another of the platens from and under control of means other than those which normally effect operation thereof, as will be explained.

Consequently, a main control and certain auxiliary controls are included in the machine and in the present instance the main control of the machine is afforded by a plurality of switches 800, Fig. 41, which embody switch discs 1026 that are fast on a shaft as 802 journaled in bearings provided in brackets as 803 and 804. The bearing afforded for the shaft 802 in the bracket 804 is releasable and further the shaft 802 is detachably connected to a shaft 805 that is vertically aligned therewith and which is journaled in bearings provided in the bracket 803. This arrangement enables the shaft 802 and the switch discs 1026 carried thereby to be removed from the machine when and as desired.

The present embodiment of my invention relates to a machine that is adapted to make duplicate impressions on each check S that is passed through the machine, which is to say, changeable data A are printed on both the main body Sm and the stub Sb of each check S as are the variable data V1 and V2. To this end, the main platen MP is operated, as described hereinabove, so as to make four reciprocations in each cycle of operation of the machine. In some instances, however, it will not be necessary that changeable data as A be printed on both the main body and the stub of a check as in an instance where the check does not embody a stub as Sb. In such an instance the machine is operated in what is referred to as a consecutive manner in contradistinction to the so-called duplicate operation of the machine in the present embodiment thereof. However, since there will be instances where it will be advantageous to optionally operate the machine in either a consecutive or a duplicate manner, I have so arranged the drive for the shaft 802 on which the discs of the main control switches 800 are mounted as to enable these switches to effect either consecutive or duplicate operation of the machine.

Therefore, as best shown in Figs. 46 and 47, a pair of gears 806 and 807 are mounted for rota-

tion about the shaft 805. These gears are respectively meshed with gears 809 and 810 of which the gear 810 is fast to the shaft 811 by a set screw 810a, while the gear 809 is mounted for rotation about this shaft 811 which is journaled in suitable bearings afforded in the bracket 803.

A keyway 812 is formed in the shaft 811 and a key 813 is disposed therein and controls connection of the gear 809 to the shaft 811. A pair of pockets 825 and 826 are formed in the key 813 and a spring-pressed detent 827 mounted in the shaft 811 may be selectively disposed in either of these pockets. When the detent 827 is disposed in the pocket 826, the key 813 is held in such a position that the cam surface 821a thereon has been effective to move the pawl as 816a in the hub of the gear 809 out of the keyway 812 and so long as the key 813 keeps the pawl 816a out of the keyway 812 the gear 809 is disconnected from the shaft 811. When, however, as shown in Fig. 47, the detent 827 is disposed in the pocket 825, the key 813 is withdrawn from cooperating relation with the pawl 816a and thereupon the spring 818a is effective to hold this pawl in the keyway 812 to thereby connect the gear 809 to the shaft 811 for rotation therewith.

Likewise, a pair of spring-pressed pawls 816 and 817 are respectively mounted in the hubs of the gears 806 and 807 and these pawls are pressed by springs 818 toward the keyway 819 in the shaft 805. When these pawls are disposed in this keyway, as shown in Fig. 46, the gears 806 and 807 are both connected to the shaft 805 for rotation therewith. Under such circumstances the key 820 in the keyway 819 in the shaft 805 is disposed in the position in which it is shown in Fig. 46 in which instance the spring-pressed detent 822 in the shaft 805 is seated in the pocket 823 in the key 820 to retain the key in this retracted position.

However, when the key 820 is moved through the keyway 819 to dispose the spring-pressed detent 822 in the pocket 824 in the key 820, then the cam surface 821 on this key is effective to force the pawl 816 out of the keyway 819 and thereupon the gear 806 is disconnected from the shaft 805.

When the machine is to be arranged for duplicate operation, the keys 813 and 820 are disposed in the position in which they are shown in Fig. 46 and thereupon the gear 809 is disconnected from the shaft 811 but the gears 806 and 807 are connected to the shaft 805. In a manner to be described presently, a gear 828 meshed with the gear 809 is driven when the switch shaft 802 is to be operated. When the gears 809, 806 and 807 are connected, as shown in Fig. 46, the gear 828 is effective to rotate the gear 809 and therefore the gear 806 and consequently the shaft 805 and therefore the shaft 802 rotates the switch disc 1026, whereupon the switches 800 are selectively closed and opened, as will be described presently. In such circumstances the shafts 805 and 802 make one revolution to two revolutions of the gear 828. Moreover, in such circumstances the gear 807 drives the gear 810 and consequently the shaft 811 is rotated but this is ineffective in such instances.

When, however, the machine is to be operated in a consecutive manner, the keys 813 and 820 are disposed in the positions in which they are shown in Fig. 47 and in such circumstances the gear 809 is connected to the shaft 811 but the gear 806 is disconnected from the shaft 805 and, while under such circumstances, the gear 809, when it is rotated, rotates the gear 806, this is ineffective in so far as operation of the shaft 805 from the gear

806 is concerned. In this instance, however, the ratio of the gears is such that the shafts 805 and 802 will make one revolution for each revolution of the gear 828 because in this instance the drive is from the gear 828 to the gear 809 and shaft 811 and through the gear 810 fast thereon to the shaft 807 which, in this instance, is connected by the pawl 817 to the shaft 805.

Thus, when the just described mechanisms are arranged in the manner shown in Fig. 46, the machine is arranged for duplicate operation but when the parts are arranged in the manner shown in Fig. 47 the machine is arranged for operation in a consecutive manner. This particular operation of the machine is described more fully hereinafter with reference to a modification of the present embodiment of the invention. Hence, it is to be understood that in so far as the present embodiment of the invention is concerned, in which the machine is arranged for duplicate operation, the parts are arranged in the manner shown in Fig. 46 so that the switch shaft 802 will make one revolution while the gear 828 makes two revolutions.

As best shown in Figs. 41, 42 and 46, the gear 828 is fast on a sleeve 829 which is rotatably mounted on the timing drive shaft 104 that is constantly rotated from the main drive shaft 90 when the machine is in operation in the manner described hereinabove. The sleeve 829 is adapted for cooperation with a collar 830 fast on the shaft 104. This sleeve and this collar constitute the separable parts of a uniformly engaging clutch MC of the kind described in my copending application Serial No. 239,563, filed November 8, 1938. This clutch is under control of a solenoid 831 which, in a manner described hereinafter, is energized at selected times in the course of operation of the machine to enable the sleeve 829 to be connected to the collar 830 so as to thereupon set the gear 828 in operation to drive the shaft 802 in the manner described hereinabove. It will be understood that since the clutch MC is a uniformly engaging clutch, the gear 828 is connected to the shaft 104 in an identical angular relation each time the solenoid 831 causes the sleeve 829 to be connected to the collar 830. Such engagement of the clutch MC is effected once for each normal cycle of operation of the machine, as is described more fully hereinafter.

It will be noted that when the machine is arranged for duplicate operation in the manner described hereinabove the shaft 805 makes one revolution in the course of each cycle of operation of the machine, and this is also true when the machine is arranged for consecutive operation. Therefore the main cam shaft 300, which controls the passage of the sheets as S through the machine and other cyclic operations of the machine, may be advantageously driven from the shaft 805. Consequently, a bevel gear as 832 is fast on the shaft 805 and meshes with a bevel gear 838 fast on a shaft 844, Figs. 41 and 43, suitably journaled in a bearing as 845 on the bracket 803 and a bearing 846, Fig. 43, provided on the bracket 847 carried by the table top TT. The shaft 844 has another bevel gear 848 thereon which meshes with a bevel gear 849 on the cam shaft 300 and the ratio of bevel gears 832—838 and 848—849 is one-to-one so that the cam shaft 300 is driven in a one-to-one ratio with the cam shaft 805.

In the manner described, for example, in Letters Patent No. 2,211,772, patented August 20, 1940, the cam shaft 300 controls the movement to and from sheet stopping position of stop fingers as

850, 851 and 852, Fig. 2, which successively operate to dispose the sheets as S in position to have the changeable data A and the variable data V1 and V2 printed thereon at the proper positions.

Moreover, a plurality of sheet feeding rollers as 854, Fig. 2, are mounted in brackets as 855 in the manner described, for example, in said Letters Patent No. 2,211,772, and these rollers are suitably connected to a shaft 856 to be driven therefrom at relatively high speed. The shaft 856 has a pulley 857 thereon about which an endless belt 858, Figs. 2 and 9, is passed, this belt also being passed about a pulley 859 fast on the main drive shaft 90, this endless belt as 858 being advantageously directed about idler pulleys as 860, Fig. 9, to be clear of certain operative mechanisms in the machine. So long as the main drive shaft 90 is in operation, the belt 858 is effective to drive the shaft 856 to thereby rotate the rollers as 854 at relatively high speed so that when a sheet is released from the sheet feeder SR to be passed into the sheet guideway SG, these rollers 854 are effective to advance the sheet through this guideway and into association with the stop fingers 850, 851 and 852.

In the present instance the sheets as S pass into the sheet guideway SG at a time when the stop finger 850 is disposed in sheet stopping position. Upon engagement of the leading edge of this sheet with the stop finger, the main body Sm of the check S is disposed in position to receive the impression of changeable data A thereon upon the first operation of the platen MP. Thereafter the cam shaft 300 retracts the stop finger 850 from sheet stopping position and brings the finger 851 into sheet stopping position, whereupon the rollers 854 advance the leading edge of the sheet into engagement with the stop finger 851 to dispose the stub Sb of the check S in position to receive the impression of changeable data A at the proper position thereon. Subsequently, the cam shaft 300 elevates the stop finger 851 from sheet stopping position and moves the stop finger 852 into sheet stopping position and thereupon the rollers 854 advance the leading edge of the sheet S into engagement with this stop finger to thereupon dispose the stub Sb relative to the main platen MP in position to receive an impression of the variable data V1 and V2 at the proper position thereon.

At this time the main body Sm of the check S will be disposed well beyond printing relation with the main platen MP and it thereupon becomes necessary to move the sheet S through the sheet guideway SG in a direction opposite to that in which it is moved by the rollers as 854. To this end a roller as 861, Fig. 24A, is provided which is under control of the cam shaft 300. This roller 861 is mounted on a shaft 862 journaled in a bracket 863 that is pivotal about and slideable on the roller driving shaft 856. The shaft 862 on which the roller 861 is mounted has a bevel gear 864 thereon that is selectively engageable with the bevel gears 865 and 866 on the shaft 856. A spring 867 is normally effective on the bracket 863 to urge the cam follower 868 on the bracket 863 into engagement with the face cam 869 fast on the cam shaft 300 and so long as the cam follower 868 rides on a dwell on the cam 869, the gear 864 is meshed with the gear 865 so that the roller 861 is driven in the same directions as the rollers 854 and is therefore effective to force an underlying sheet S toward the stop fingers as 850.

When, however, the variable data V1 and V2

have been printed on the stub Sb of a check S and it is necessary to bring the main body Sm of the check back into position to have the variable data V1 and V2 printed thereon, the cam follower 868 moves onto a rise on the face cam 869 and shifts the bracket 863 to disengage the gear 864 from the gear 865 and to move it into engagement with the gear 866 and thereupon the roller 861 is rotated in a direction opposite to that in which the rollers 854 are rotated. At this same time an arrangement of the character, for example, disclosed in Letters Patent No. 2,211,772, patented August 20, 1940, including a cam as 870, Fig. 24A, acts on a cam follower as 871 on each bracket 855 for those rollers 854 that are disposed in position to engage the sheet as S when it is associated with the main platen MP and thereupon these particular rollers 854 are raised from engagement with the underlying sheet S, which is therefore only acted upon by the roller 861 which at this time, as explained, is rotating in a direction opposite to that in which the rollers 854 rotate. Consequently, the roller 861 forces the sheet S back through the sheet guideway SG into engagement with the stop 872, Fig. 2, in the sheet guideway SG.

The stop 872 has a leaf spring as 873 thereon that extends into the sheet guideway in such a manner that the rollers 854 may be effective to advance a sheet thereby through the sheet guideway. However, the spring 873 is effective, when the sheet is moved by the roller 861 when it is rotating reversely, to guide what was the trailing edge of the check into engagement with the stop 872. When this edge of the sheet engages this stop, the sheet is disposed in such position as to enable the main platen MP to cause the variable data V1 and V2 to be printed on the main body Sm of the check at the proper position thereon.

If the roller 861 remained in a position to be effective on the check S at a time when it is engaged with the stop 872, as aforesaid, there might be a tendency to buckle the check which might impair the printing operation to be effected thereon. Consequently, as soon as the aforesaid trailing edge of the check has engaged the stop 872, the cam 874 on the cam shaft 300, Fig. 24A, acts on a cam follower 875 on the bracket 863 to pivot this bracket about the shaft 856 in such a manner as to move the roller 861 upwardly out of engagement with the check as S. During the time the roller 861 is retained in this upper position, the cam follower 868 moves back onto the dwell on the cam 869 and thereupon the spring 867 slides the bracket 863 on the shaft 856 to disengage the bevel gear 864 from the bevel gear 866 and to reengage it with the bevel gear 865 and thereupon the roller 861 again starts to move forwardly. Thereafter the cam 874 enables the bracket 863 to so pivot that the roller 861 may again move into engagement with an underlying check S and at this time the cams as 870 also enable those rollers 854 which were elevated out of engagement with the check S to move back into position to engage an underlying sheet. This occurs at a time subsequent to the printing of the variable data V1 and V2 on the main body Sm and consequently the check S bearing two impressions of changeable data A and two impressions of variable data V1 and V2 is advanced forwardly through the sheet guideway SG to the printing unit PC, Fig. 1.

The sheet S is thereafter admitted at the proper time into the printing couple PC wherein, if necessary, the form C is printed on the sheet, as also

are the date E, signature Sn and the like. After passage through the printing unit PC the sheet is discharged into the sheet collector SC.

Each check S that passes through the machine has the number N printed thereon and a corresponding number N1 is printed on the proof sheet as PS1 in association with the variable data V1 and V2 and changeable data A printed thereon from or under control of a particular printing and control device. I therefore provide conventional accumulating number printing units 880 and 881, Fig. 25, respectively in association with the main platens MP and PP. In the present instance these numbering units are carried by brackets 882 and 883 fast to the outwardly disposed face of the side frame member 505. Each numbering unit includes an operating arm as 884 and these arms are interconnected through a link 885 to insure conjoint operation of the arms 884 which, in the manner well understood in the art, function to advance the numbering unit in a consecutive step-by-step manner each time they are operated.

In the present instance the numbering units 880 and 881 are to be advanced each time the multiplying mechanism M is set in operation for this mechanism makes a complete operation for each check as S and each printing of aligned data A and V1 and V2 on a proof sheet as PS1. To this end a link 886, Fig. 25, is connected to the operating arm 884 of the numbering unit 880 and to the arm 887 of a bell crank 888 suitably mounted on the frame member 505, as indicated at 889. The arm 890 of the bell crank 888 carries a roller 891 that cooperates with a peripheral cam 892 fast on the cam shaft 499 of the multiplying mechanism M. In the course of an operative rotation of the cam shaft 499 this cam causes an advancing of the numbering units 880 and 881 one digital amount so as to enable consecutively numbered impressions to be made therefrom.

When a printing and control device is selected to be printed, the main platen MP makes four reciprocations, as has been explained hereinabove. In each such reciprocation of the main platen MP it is effective to push a Bowden cable which, in turn, operates a delay mechanism which enables the printing face 302 of the platen PP to remain effective when the printing and control device disposed at station III, when the platen MP makes such four reciprocations, attains station V. To this end a sheathing about a Bowden cable 1280, Fig. 24C, is secured to a bracket 1281 in such position as to enable the adjacent end of the Bowden cable to be connected to a lug 1282 on the main frame 219 of the platen MP. Therefore, each time the platen MP makes a reciprocation, the Bowden cable 1280 is pushed and retracted. In dependence upon whether or not this Bowden cable is pushed, counting means in a delay mechanism, to be described presently, are disposed in effective or ineffective position, such counting means being advanced to the operative positions thereof by reciprocations of the rocker 150, Fig. 10, which effects reciprocation of the carrier bars 121 and 122, as explained hereinabove.

The delay mechanism to which reference has just been made is best shown in Figs. 10 and 12 and includes a hub 1283 that is rotatably mounted on a shaft 1284 carried by the bracket 111. A ratchet 1285 is provided on the hub 1283 in position to be engaged by a pawl 1286 pivotally mounted on the rocker 150, as indicated at 1287.

A spring 1288 is effective on one end of the pawl 1286 to urge the opposite end thereof toward the teeth of the ratchet 1285. In each reciprocation of the rocker 150 to effect a reciprocation of the carrier bars 121 and 122 and advancing of printing and control devices, the pawl 1286 moves from engagement with one tooth of the ratchet 1285 and into engagement with the succeeding tooth and advances the ratchet 1285 one tooth space. A retaining pawl 1289 is carried by the bracket 1290 on the bracket 111 and is effective to prevent retroactive movement of the ratchet 1285. In this respect it is to be noted that the rocker 150 makes one reciprocation for each two reciprocations of the main platen MP in a cycle of operation in which this main platen MP is operated.

The aforesaid counting arrangement comprises the pins 1291 that are mounted at spaced apart intervals in the hub 1283. In each advancing of the hub 1283, effected by the pawl 1286, one of these pins is brought into alignment with the adjacent end of the Bowden cable 1280, that is, the end thereof opposite that connected to the platen MP, the sheathing about the Bowden cable 1280 adjacent said end of the cable being anchored to the bracket 1290 to retain this end of the cable in the aforesaid position.

This arrangement is such that each of the first two reciprocations of the platen MP are effective through the Bowden cable 1280 to push one of the pins 1291 from the normal position of such a pin where it depends from the upper flange of the hub 1283. In the event any one of the pins 1291 is so pushed in the course of the step-by-step advancing of the hub 1283, such pin moves into engagement with a cam plate 1295, Fig. 12, to be restored to its normal depending position after passing through operative position at the switch 1292.

Hence, intermediate the point whereat the pins 1291 are pushed upwardly by the Bowden cable 1280 and that whereat they are restored to their normal depending position by the cam plate 1295, those pins 1291 which are not pushed upwardly by the Bowden cable 1280 remain in their depending position and engage a blade 1293 of a switch 1292 and force a contact on this blade into engagement with a contact on the blade 1294 of this switch to thereby close the switch which in all instances where it is not engaged by a pin 1291 is open.

In this respect while two pins as 1291 are pushed in each four reciprocations of the platen MP that are effected in a normal operation thereof where a printing and control device is selected to be printed, it is the first of such pins to reach the switch 1292 that is effective, in so far as the normal operation of the machine is concerned. Two such pins are provided, to enable the intended operation of the machine to be effected, for example, where the printing and control devices pass through the machine one after the other without having impressions made therefrom. Moreover, the aforesaid arrangement of the pins insures that the delay device that is afforded by the hub 1283 and the pins 1291 carried therein will not get out of step with other operative mechanisms in the machine.

The first of two unpushed pins does not effect closure of the switch 1292 until two reciprocations of the carrier bars 121 and 122, subsequent to those effected in the cycle of operation in which pins as 1291 were not pushed in a cycle of 70 operation in which the main platen MP is not

operated. In the two reciprocations of the carrier bars 121 and 122 that thus intervene between the time the pins 1291 are pushed or not pushed and closing of the switch 1292 when it is engaged by an unpushed pin, a printing and control device which has been disposed in station III is advanced to station V.

The particular manner in which the delay mechanism, including the pins 1291 which are pushed or not pushed as aforesaid, is utilized in the course of operation of the machine is described fully hereinafter with reference to the effect of a selection of a printing and control device to be passed through the machine without having impressions made therefrom.

PAGER AND PROOFER

The pager and proofer mechanism PM is normally enclosed within a housing as shown in Fig. 1, and the mechanism of the pager and proofer is carried within the housing by a frame 900. The frame 900 comprises a pair of side plates 901 and 902 spaced apart by connecting bars 903 and 904, and the mechanism of the pager and proofer is mounted on or between the two side plates 901 and 902. The frame 900 is supported along the forward edge of the main frame of the machine by a horizontal supporting bar 905 secured to the machine frame and engaged with slots 906 in the adjacent edges of the side plates. Additional support for the frame 900 is provided by a bracing bar 907 extending downwardly from the frame 900 and connected to the main frame. Further support is provided by a connecting link 908 extending from the roll supporting structure 308 to an upper portion of the frame 900.

The web W which is utilized in forming the proof sheets is withdrawn from a roll R supported in front of the machine on an axis which is generally parallel to the line of movement of the web W past the platen PP, and the web is therefore led upwardly about a guide roller 989 and then in a horizontal direction beneath an angular guide bar 910. The guide bar 910 is disposed between the two side plates 901 and 902 in a horizontal position and at an angle of 45° to the side plates. The web is then led in a rearward direction about the guide bar 910 and toward and under the platen PP so that the web may then extend upwardly about the two guide rollers 306 and 307. The web W extends in a forward and downward direction from the guide roller 307 and is led to web advancing means disposed between the two side plates 901 and 902. The web advancing means in the present instance comprises a lower feed roller 911 which is engaged on its upper side by a pressure roller 912. The web W is led under the feed roller 911 and about this feed roller so as to pass between the feed roller and the pressure roller 912. The web is then led upwardly along the rear face of a feed roller 913 and then rearwardly between the feed roller 913 and an upper pressure roller 914. The web then extends in a forward direction so as to pass beneath a severing means such as a knife 915. In the operation of the pager and proofer the web is advanced step by step so that the end thereof moves past the knife 915 and into position over a collecting tray 916 into which the severing sheet falls when the knife 915 is operated.

Means is provided for operating the web advancing or line spacing means and the knife 915 in proper timed relation to the other mechanisms of the machine, and since the pager and proofer is not employed in every use of the present ma-

chine a separate drive motor 95PM is provided for actuating the various operative mechanisms of the pager and proofer. The motor 95PM is mounted beneath the frame 900 as shown in Fig. 52, and a belt 917 connects the motor to a pulley 918 mounted on the side of the side plate 902, Fig. 53. The pulley 918 is connected to a pinion 919 which meshes with a gear 920 rotatably mounted on the projecting end of a cross shaft 921. The cross shaft 921 is utilized to actuate the various mechanisms of the pager and proofer, and when such actuation is required, the gear 920 is clutched to the shaft 921 by the operation of a one-revolution clutch 922. The one-revolution clutch 922 may be of the type disclosed in my aforesaid copending application Serial No. 239,561, filed November 8, 1938. When the clutch 922 is to be engaged for operation through its one-revolution cycle, a control solenoid 923 is momentarily energized as will hereinafter be described.

At its other end the cross shaft 921 has a radial arm 924 fixed thereto and this arm has one end of a link 925 connected thereto. At its other end the link 925 is connected to the end of a rocking arm 926 rotatable about the axis of the roller 913. A pawl 927 carried on the rocking arm 926 is spring-biased into engagement with the edge of a ratchet wheel 928 which is fixed to the roller 913. Thus in each revolution of the cross shaft 921 the ratchet and pawl mechanism is operated to advance the feed roller 913 through a web advancing or line spacing movement.

This pager and proofer mechanism PM is adapted to sever the web to form sheets which carry a predetermined number of lines of data A and V, and means is therefore provided to operate the knife 915 to produce sheets bearing the desired number of lines. To this end a counting mechanism is employed to set the knife-operating mechanism in operation in a particular cycle of operation of the web advancing means. The operating means for the knife 915 includes a bell crank 930 upon one arm of which the knife 915 is carried. The other arm of the bell crank 930 carries a cam follower 931 which bears against a cam 932. Such engagement of the follower 931 with the cam 932 is caused by spring return means 933 associated with the bell crank 930. The cam 932 is rotatably mounted on the cross shaft 921 adjacent to the side plate 901, and when the knife 915 is to be actuated through a web severing cycle, the cam 932 is connected to the cross shaft 921 for rotation therewith. For this purpose a one-revolution clutch 934 is interposed between the cross shaft 921 and the cam 932. This clutch may be of the kind disclosed in my aforesaid copending application Serial No. 239,561, filed November 8, 1938. When the clutch 934 is to be engaged for operation through its one-revolution cycle, a control solenoid 935 is momentarily energized in a manner to be hereinafter described.

As hereinbefore pointed out the web severing knife 915 is operated after a predetermined number of impressions or lines have been printed upon the web, and this result is accomplished through a counting mechanism which controls the energization of the solenoid 935. In the present instance this counting mechanism comprises a ratchet wheel 936 mounted on the outer side of the side plate 901 on a mounting stud 937. This ratchet wheel 936 has a rocking arm device 938 associated therewith, there being a pawl 939 on the rocking arm device whereby the rocking

arm device engages the ratchet wheel 936 to operate the same. The rocking arm device 938 has a tensioning spring 940 which acts on one end of the rocking arm so as to maintain the other arm against the arm 924. Thus in a rotative movement of the arm 924 the rocking arm device 938 is actuated to index the ratchet wheel 936 through a predetermined angular distance. After a predetermined number of web advancing movements, a pin 942 projecting from the ratchet wheel 936 engages one spring arm of a normally open switch 943 which is carried on a mounting bracket 944 as illustrated in Fig. 52A. When the pin 942 closes the switch 943 a circuit to the knife control solenoid 935 is conditioned for closure. Such closure of the circuit to the knife control solenoid 935 is effected in the next operation of the web advancing means, as will be described hereinafter.

The counting mechanism which includes the ratchet wheel 936 is also utilized for controlling other operations of the machine and to this end a sleeve 945 is fixed to the ratchet wheel 936 so as to project along the stud 937 in surrounding relation thereto. This sleeve 945 carries control means whereby other control switches are actuated in the course of operation of the counting mechanism. It will be recalled that the present machine is arranged to print a sheet total at the end of each portion of the web which is subsequently to be severed to form a sheet, and the counting mechanism which includes the ratchet wheel 936 is utilized to institute operation of the total taking mechanism in proper timed relation to print a sheet total or page total PTT at the proper point on the web. The counting mechanism also is utilized to cause the machine to stop when such a total is being taken and printed, as explained hereinafter. Since the printing of the page total PTT involves a further line spacing movement of the web W, ratchet wheel 936 is formed with one tooth for the total printing operation and one tooth for each line of data A and V which is to be included on a page, so that the ratchet wheel completes its rotative cycle only after completion of the total printing cycle. In the present instance the pager and proofer PM is constructed so as to produce pages having twenty lines of data A and V, so that the counting ratchet wheel 936 embodies 21 teeth, as shown in Fig. 52.

In attaining the desired total printing and machine stopping operations under control of the counting mechanism, a pair of switches 946 and 947 are mounted in the path of an arm 948 fixed on the sleeve 945. When the arm 948 engages a block 949 on the upper blade of the switch 946, the upper blade is pressed downwardly so as to close the switch 946, and through the medium of an insulating block 950 interposed between the two switches, the switch 947 is also closed. The arm 948, however, rides over a high point on the block 949 and comes to rest in a notch 951 thereby allowing the switch 947 to open while switch 946 is maintained closed. The switch 947, which is momentarily closed, is utilized to cause the machine to be stopped in so far as its primary or normal functions are concerned, while the switch 946 is utilized to institute a total taking operation as will be hereinafter described.

The sheet total which is obtained by the operation of the total unit is set up in the type segments TS2, and since the web W has been advanced since the printing of the last variable

data V, the sheet total will be printed in the next line of the web. At the time the total is printed, the printing and control device D from which the last-printed variable data were derived is at rest at printing position, and hence the changeable data A are printed therefrom in line with the corresponding variable data V, this impression A being made concurrently with the printing of the total.

It will be recognized that when a total is to be printed at the end of a sheet, the printing device feeding means will be inactive, and the printing device from which an impression A is made in the last line, as aforesaid, will remain in position beneath the platen face 301 at the end of the total printing cycle. Means are, therefore, provided for causing the platen face 301 to be receded to its ineffective position in the cycle which follows a total printing cycle, so that in this cycle merely the variable data and the number N are printed in the line which is to constitute the first line of the next page or sheet. This means includes a switch 953 mounted on the bracket 944 and adapted to be closed by an arm 954 fixed on the sleeve 945. The arm 954 is so disposed upon the sleeve 945 that the switch 953 will be closed at the end of or late in the total printing cycle, and the switch 953 is arranged when closed to provide an energizing circuit to the solenoid 327. This solenoid shifts the abutment arm 323, beneath the roller 319 so that as the platen PP moves through its printing stroke in the next cycle of operation, the cam shafts 314 are rocked so as to permit upward shifting movement of the printing face 301 relative to its support 310. Thus the pager and proofer mechanism PM and the sectional proof printing platen PP cooperate in attaining proper distribution and arrangement of the totals as well as the other classes of data.

In such a total printing operation of the platen PP the circuit to the control solenoid 342 is not closed, and therefore the printing face 304 which serves to print the number N on the proof sheet remains in its inactive position thereby to avoid printing a number opposite the total on the sheet. In certain operations of the present machine, as for example, in those instances where a ledger total is to be printed, the machine also operates to print a sheet total prior to the printing of the ledger total, and in such instances it is desirable to reset the counting mechanism which includes the ratchet wheel 936. Suitable manual means such as a knob on the end of the sleeve 945 are provided whereby the counting mechanism may be reset so as to produce a sheet of the proper length in the next operation of the knife 915.

ACCUMULATOR

In an instance such as the present one where it is desired to print totals on the web W to appear at the bottom of each proof sheet as PS1 into which the web W is divided by the pager and proofer mechanism PM and where it is also desired to print ledger totals on the proof sheets and also a grand total, I provide three accumulators AC-PT, AC-LT and AC-GT, Fig. 27, in the printing unit 600, these accumulators in the present instance being of the kind shown and described in my aforesaid copending application Serial No. 221,841, filed July 28, 1938, now issued as Patent No. 2,296,277, patented September 22, 1942, and being respectively operable to enable page totals, ledger totals and grand totals to

be printed on the web W when the need so to do arises in the course of operation of the machine.

The accumulators AC-PT, AC-LT and AC-GT are mounted in a frame comprising side plates as 700 and 701, Figs. 27, 32 and 33, which are respectively disposed in juxtaposition to, and which are respectively secured to, the side frame members 504 and 505, as best shown in Fig. 33. Each accumulator as AC-GT also comprises a frame including frame members 707 and 708, Figs. 32 and 33, in which a shaft as 704 is journaled. A plurality of accumulator wheels as 705 are rotatably mounted on the shaft as 704, and these accumulator wheels are respectively aligned with the slide sections 555 f and these accumulator wheels, which are in the form of gears, are adapted to mesh with a rack as 706, Fig. 27, on the particular slide section 555 f that is aligned therewith. In this respect it is to be noted that structurally each of the accumulators AC-PT, AC-LT and AC-GT correspond structurally and that the accumulator wheels respectively included therein are aligned one with the other so that the accumulator wheel as 705 in each accumulator, which relates to the units order therein, is aligned with the accumulator wheels in the other two accumulators that also pertain to the units order. These aligned wheels are also adapted for cooperation with the slide section 555 f which pertains to the units order, and this is true with respect to each slide section as 555 f and the aligned accumulator wheels in the respective accumulators. Therefore, the rack as 706 on the lower edge of each slide as 555 f is sufficiently prolonged as to extend over each of the accumulator wheels in the respective accumulators that are adapted for cooperation therewith wherefore when any one of the accumulator wheels is moved upwardly, in a manner to be described presently, the accumulator wheels therein as 705 will mesh with the racks 706 on the associated slide sections 555 f .

The manner in which the accumulator as AC-GT is constructed and is operated to be moved upwardly to bring the teeth on the accumulator wheels 705 thereof into mesh with the racks as 706 respectively associated with such wheels is described in detail herein and it is to be understood that this is typical of the construction and operation of the other two accumulators. Thus, the frame members 707 and 708 of the accumulator AC-GT and the parts mounted between these frame members are moved upwardly upon operation of cam plates as 702 and 703 mounted outwardly of and adjacent to these frame members 707 and 708. These cam plates have cam slots as 709, Fig. 27, therein that are of a configuration much like that of the cam slot 535, Fig. 26, and upon rocking of the cam plates about the pivotal supports therefor, described presently, these cam slots are effective to move the shaft 704 upwardly in the guide slots as 712 and 713, Fig. 33, provided therefor in the side plates 700 and 701 and to this end the cam plates 702 and 703 are pivoted about the shaft 710 on which they are pivotally mounted. The shaft 710 is carried by a pair of arms 714 and 715, Fig. 32, which, in turn, are pivoted on the shaft 716 journaled in the side plates 700 and 701. The shaft 710 is supported in position between a pair of adjusting screws 717 and 718, Fig. 32A, respectively disposed in ears 719 and 720 on a plate 721 on a rocker 722 that is pivotally mounted on the shaft 716.

The rocker 722 includes a hub 723, Figs. 32A

and 33 that is disposed about one end of the shaft 716 that is journaled in bearing the side plates 708 and 701, as best shown in Fig. 33. A spring 724, Fig. 33, confined in this hub is normally effective to dispose the arm 725 of the rocker 722 in the intermediate position in which it is illustrated in Fig. 33, which is to say, to dispose the gear segment 726 at the upper end of this arm in a position intermediate the two racks as 727 and 728 that are mounted on comb brackets 729 and 730, Fig. 25, fast to the outwardly disposed face of the side frame member 505, which racks are adapted to be reciprocated in the comb brackets 729 and 730, in a manner described presently.

When, however, the accumulator wheels 705 are to be meshed with their associated racks 706, the rocker 722 is moved either against or under the influence of the spring 724 to bring the gear segment 726 thereon into mesh with either the rack 727 or 728 in a manner explained herein-after. In this respect the gear segment 726 is meshed with the rack 727 when an amount is to be entered into the accumulator AC-GT and is meshed with the rack 728 when a reading is to be taken from the accumulator for the purpose of setting up the type segments TS2 to enable the accumulator total to be printed, in a manner to be described presently. Therefore, the spring 724 forces the end of the hub 723 into engagement with an adjustment screw 731 mounted in the arm 732 of a bell crank lever 733 which includes a hub 734 that is mounted on a shaft 735 carried by suitable brackets as 737, Figs. 32 and 33, fast to the side frame member 505.

In a manner to be explained presently, the bell crank 733 is pivoted clockwise, as viewed in Fig. 33, when the gear segment 726 is meshed with the rack 727 and thereupon under the influence of the spring 724 the rocker 722 shifts to the left, as viewed in Fig. 33, to mesh the gear segment 726 with the teeth of the rack 727. Thereafter, upon actuation of the rack 727, in a manner to be explained presently, the rocker 722 and therefore the plate 721 and the ears 719 and 720 thereon are pivoted upwardly, as viewed in Fig. 32A, to be effective through the adjustment screws 717 and 718 to move the shaft 710 upwardly. This is effective through the cam slots as 709 to move the shaft 704 upwardly in the guide slots 712 and 713, Fig. 33, whereupon the accumulator wheels 705 are engaged with their associated racks 706. Manifestly upon movement of the bell crank 733 counterclockwise in a manner to be described presently, the spring 724 is compressed and thereupon the rocker 722 is disengaged from the rack 727, and this is effected after the rack 727 has been actuated to restore the accumulator wheels 705 to the position in which they are shown in Fig. 33 out of engagement with the racks 706. This restoration is effected either after an entry has been made into or a readout has been made from the accumulator wheels 705, as will be described presently.

When the accumulator wheels 705 are disposed in their lower position shown in Fig. 33, they are engaged with carry segments as 738, Figs. 27 and 33, which are of the character and which are operated in the manner described in my aforesaid copending application Serial No. 221,841 to effect a carry from any one accumulator wheel to the accumulator wheel for the next higher order when the need so to do arises in the course of entries into the accumulator wheels.

In order to insure proper vertical movement of the frame including the frame members 707 and

708, these frame members are interconnected by a tie bar as 711, Fig. 33, and the frame member 708 includes a depending portion 739 which has a bifurcation 740 therein that embraces the shaft 710 to thereby guide the frame, of which the frame members 707 and 708, are a part in the course of vertical reciprocation thereof.

In the present machine, accumulator wheels as 705 included in the accumulator AC—PT are to receive entries from the slide sections 555f each time these slide sections are operated to set up the type segments TS2 to enable variable data V1 and V2 to be printed on a proof sheet as PS1. Moreover, a sufficient number of accumulator wheels as 705 are included in this accumulator AC—PT, as well as each other accumulator, to care for carry-overs from lower orders so that there is a greater number of accumulator wheels as 705 in each accumulator than there are slide sections 555f which are effective to set up the type segments as TS2 from devices operated under control of the multiplying mechanism M. However, slide sections as 555f are associated with these additional accumulator wheels in each accumulator in order that totals accumulated in the accumulators may be read out therefrom and utilized for the purpose of setting up type segments TS2, in those operations where totals are to be printed on the web W.

Each time the type segments TS2 are set up under control of the multiplying mechanism M, in the manner described hereinabove, entries are made only into the accumulator AC—PT, from which totals are printed at what is to be the last item on each proof sheet into which the web W is divided, as will be explained. This is effected during the restoration of the slide sections 555f in each operation during which the type segments are set up as stated, under control of the multiplying mechanism M.

Therefore, the rocker as 722, Fig. 33, included in the accumulator AC—PT is normally disposed in such position that the segment 726 thereon is meshed with teeth on the rack slide 727. During the time slide sections 555f are being moved to set up the type segments TS2, the rack 727 is in such position that the shaft as 710 in the accumulator AC—PT is disposed in its lower position so that the accumulator wheels 705 in this accumulator are disengaged from the racks 706 on the associated slides 555f. However, intermediate the end of the rearward movement of the slide sections 555f to set up the type segments TS2 and the time at which these slide sections are moved forwardly to be restored to their normal at rest positions, the rack 727 is actuated in a manner to be described presently to cause the shaft as 710 in the accumulator AC—PT to be moved upwardly to thereby engage the teeth on the accumulator wheels 705 with the racks 706 so that, in the course of restoration of the slides 555f, whatever digital amounts these slides have been set to represent are entered into the associated accumulator wheels 705 of the accumulator AC—PT. As stated, any carries that may be required from lower orders to higher orders are effected as an incident to such entries from the slide sections 555f by carry-over devices of the kind described in my aforesaid copending application Serial No. 221,841, now issued as Patent No. 2,296,277, patented September 22, 1942, but in this respect it is to be understood that any suitable carry devices might be utilized for this purpose.

It will, therefore, be seen that the rack 727

must be reciprocated in the comb plate support therefor in the course of each operation of the printing unit 600 to regulate the position of the shaft 710 and the accumulator wheels 705 in the accumulator AC—PT. To this end a pair of spaced-apart lugs 745, Fig. 25, are mounted on the rack 727 and a roller 744, Figs. 25 and 33, is disposed therebetween. The roller 744 is mounted at one end of a lever 743 that is pivotally mounted on a stud shaft 745a, Fig. 33, supported by the adjacent side frame member 505. The lever 743 also has a roller 742 thereon which is urged toward the periphery of a cam 741 on the cam shaft 560 of the printing unit 600, a spring 743a, Fig. 25, being effective to maintain the roller 742 in engagement with the periphery of this cam.

In the course of a rotation of the cam shaft 560 the cam 741 is effective through the lever 743 to slide the rack 727 toward the left, as viewed in Fig. 25, and this occurs at a time in the course of operation when the accumulator wheels as 705 in the accumulator AC—PT are to be engaged with the rack 706 as aforesaid. As soon as the rack slides 555f have been restored to their at rest positions so that the digital amounts they have been set to represent will have been entered into the accumulator AC—PT, the cam 741 is effective through the lever 743 to restore the rack 727 to its at rest position to thereby be effective through the rocker 722, Fig. 24A, in the accumulator AC—PT to lower the shaft 710, included in this accumulator, to thereby retract the accumulator wheels 705 from engagement with the racks 706.

In the present machine a total is read out from the accumulator AC—PT after twenty impressions of variable data V1 and V2 have been printed on the web W for each proof sheet, as PS1 into which the web W is divided, is normally to have twenty items thereon. Therefore, in the normal operation of the machine, in a manner described hereinafter, all operative functions in the machine, except those which are required to bring about printing of a total after twenty items have been printed on the web W are suspended, as will be explained hereinafter, and means are rendered effective to enable a total to be read out from the accumulator AC—PT. In the course of reading out this total, the type segments TS2 are set up so as to enable this total to be printed on the web W immediately after the twentieth of the aforesaid twenty items, as indicated at PTT, Fig. 5. Moreover, whatever total is read out of the accumulator AC—PT is entered into the accumulators AC—LT and AC—GT.

In this respect, it will of course be understood that when the machine is initially set in operation, all of the accumulators are zeroized and in order that a page total as PTT will be printed after every twenty items, a counting arrangement such as that referred to hereinafter, which is of the character shown and described in my aforesaid copending application Serial No. 320,778, filed February 26, 1940, is included in the pager and proofer mechanism PM, this being one convenient manner of bringing about closing of a circuit to devices that are operative to cause a total to be read out from the accumulator AC—PT. It will be understood, however, that resort could be had to any convenient counting mechanism, located as desired, to bring about the printing of a page total as PTT after a predeter-

mined number of items have been printed on the web as W.

The particular manner in which a circuit such as the foregoing is closed in the present instance after twenty impressions have been made on the web W as aforesaid is described hereinafter but, in the present machine, circuit is closed to the solenoid 146, Fig. 33, normally from a switch in the pager and proofer mechanism PM, as will be explained. Upon energization of the solenoid 146, the armature 147 thereof is attracted downwardly and this is effective through the link 148 to pivot the plate 749, Figs. 32B and 33, about the shaft 750, the link 148 being pivotally connected to the plate 749, as indicated at 751. The shaft 750 is journaled in bearings provided on the brackets as 731 to be supported from the main side frame member 505. Upon such pivoting of the plate 749, the pawl 752 thereon moves into engagement with the tooth 753 on the disc 754 fast on the shaft 750, this being done for a purpose to be explained presently, the shroud 755 carried by the shaft 750 being effective to prevent the pawl 752 from engaging the tooth 756 on the disc 754 at this time. Such engagement of the pawl 752 with either the tooth 753 or the tooth 756 is effective to rotate the shaft 750 and it is this that causes the accumulator to be conditioned to enable the required operations to be performed.

Thus each accumulator includes a rocker as 722 which, as referred to hereinabove, may be moved either under the influence of or against the influence of a spring as 724, Fig. 33. It is such movement of the rocker as 722 that causes the segments as 726 on the rocker 722 to be selectively engaged with teeth on the racks 721 and 728. The effect of each spring 724 is resisted by an adjusting screw 731 which is utilized to enable the rocker 722 in the accumulators AC-LT and AC-GT to be adjusted to a proper normal position intermediate the racks, as shown in Fig. 33, and such adjusting screw 731 is also utilized to enable the rocker 722 in the accumulator AC-PT to be disposed in such a proper position that the gear segment 726 thereon is normally engaged with the teeth of the rack 721. The adjustment screws as 731 are carried by the arms 731a of bell crank levers as 733, there being one such bell crank lever for each accumulator. These bell crank levers are carried by a shaft 735, journaled in bearings in the aforesaid brackets as 731, to enable the adjustment screws 731 carried thereto to be aligned with the hubs 723 of the rockers 722 with which such screws respectively cooperate. Each such bell crank 733 also has a roller as 758 rotatably mounted on the arm as 760 thereon and these rollers cooperate with cam plates as 757 fast on the shaft 750. It is these cam plates that determine the positions to be assumed by the rockers as 722 relative to the racks 721 and 728 through the intermediary, as explained above, of the adjustment screws 731.

Normally the rockers 722 in the accumulators AC-LT and AC-GT are to be disposed intermediate the racks 721 and 728 and therefore the cam plates 757 that control the positions of these two rockers each has a dwell thereon which, when engaged by the cooperating roller 758, disposes the rocker 722 in the aforesaid intermediary position. Likewise, the cam plate 757 associated with the accumulator AC-PT has a dwell thereon which, when engaged by the associated roller 758, is effective to dispose the rocker 722 in this accumulator in position to have the gear segments 75

726 thereon meshed with the teeth of the rack 721. The cam plate 757 associated with the accumulator AC-GT has an arm 726a thereon and a spring 762 extends between this arm and a spring anchor carried by the adjacent of the brackets 731. This spring is effective to dispose the aforesaid dwells on the cam plates 757 in their normal at rest position, wherefore the shaft 750 and cam plates are disposed in a normal at rest position, the effect of this spring and therefore the aforesaid normal at rest positions being determined by the engagement of the adjusting screw 761 with the shaft 735, this adjusting screw being mounted in an ear 761a on the cam plate 757 for the accumulator AC-GT.

Therefore, when the solenoid 146 is energized, as above described, and the link 148 connected to the armature thereof is moved to cause the pawl 752 to engage the tooth 753, the shaft 750 and the cam plates as 757 thereon are rotated counterclockwise, as viewed in Fig. 33. Thereupon the aforesaid dwells on the cam plates move from engagement with the respective rollers 758, and the configuration of these cam plates is such as to dispose the rockers 722 in the desired positions.

Thus, when a page total as PTT is to be printed, the cam plates 757, when moved as just described, are effective to disengage the gear segments 726 on the rocker 722 in the accumulator AC-PT from the teeth of the rack 721 and to dispose this gear segment in engagement with the teeth of the rack 728. At this same time the rockers 722 in the accumulators AC-LT and AC-GT have the gear segments as 726 thereon meshed with the teeth of the rack 721. When the rockers 722 are disposed in these positions the operation of printing a total under control of the accumulator AC-PT may proceed.

The cam shaft 560 of the printing unit 600 is caused to make a complete revolution when a total is to be printed. To this end a bracket 763 is fast to the link 148 and carries an adjustment screw 764 which, when the link 148 moves downwardly upon energization of the solenoid 146, is effective to close switches in a switch pile 765, and it is this that sets the cam shaft 560 in operation in those instances where page totals or ledger totals are to be printed.

In the course of an operation in which a page total is to be printed, the cam 766 on the cam shaft 560 first acts on the roller 767a to thereupon actuate the lever 767, pivotally mounted on the stud 745a. When the lever 767 is so pivoted, the roller 768 thereon, disposed between lugs on the rack 728 is effective to so move the rack 728 that the accumulator wheels 705 in the accumulator AC-PT are meshed with the rack 706 on the aligned slide sections 555f. Thereafter the cam 590 on the cam shaft 560 causes the bail 585 to move to the left, as viewed in Fig. 27, whereupon the front slide sections 555f, which at this time are disconnected from the rear slide section 555r, are freed to the effect of the springs 592. Thereupon, under control of the accumulator wheels 705 in the accumulator AC-PT the slides 555f are set to represent digits represented by the positions of the wheels 705. This is effective to dispose the type characters TCf on the type segments TS2 in such position that upon operation of the platen 70 PP at this time a page total as PTT will be printed on the web.

In the course of so setting up the type segments TS2, those accumulator wheels 705 in the accumulator AC-PT, which were set to represent significant digits, return to zero position. To this

end and as best shown in Fig. 32, each rocker 722 has a pin as 975 fast therein. When a rocker as 722 is pivoted in the manner above described, to have the gear segment 726 thereon meshed with the teeth of the rack 728, the pin 975 thereon moves into engagement with a lug 976, Figs. 27 and 32, that depends from a comb plate 977. Thereupon the teeth carried by this comb are moved into position to cooperate with thickened teeth of the accumulator wheels 705 that are disposed at the zero positions thereon. Thus, when the rocker 722 in the accumulator AC—PT is disposed to engage the gear segment 726 thereon with the teeth of the rack 728, when a page total is to be printed as aforesaid, the teeth on the associated comb plate 977 are disposed in position to insure that the accumulator wheels of this accumulator will come to rest in, or will be retained in, zero position as aforesaid.

After the accumulator wheels 705 in the accumulator AC—PT have been returned to zero to thereby set up the type characters TC_f on the page segments TS₂ to enable a total as PTT to be printed therefrom, the cam 766 so actuates the lever 761 that, thereupon, the rack 728 acts through the gear segment 726 on the rocker 722 of the accumulator AC—PT to lower the shaft 710 and therefore the accumulator wheels 705 in this accumulator are withdrawn from engagement with the racks 706 on the slides 555_f. The slides at this time, however, remain in the digit representing positions into which they were moved in the course of setting up the type segments TS₁ to print a total as PTT. Therefore, substantially simultaneously with this, the cam 741 actuates the lever 743 to so move the rack 727 that the gear segments on the rockers 722 in the accumulators AC—LT and AC—GT are effective to elevate the shafts 710 and then the accumulator wheels 705 in these two accumulators move into engagement with the racks 706 on the slides 555_f which are in the digit representing positions thereof, as aforesaid. Thereafter the cam 590, Fig. 27, causes the bail 585 to restore the slides 555 to their zero positions and in so doing the racks 706 on the slides 555_f enter into the accumulator wheels of the accumulators AC—LT and AC—GT whatever digital amounts these slides have been set to represent. Therefore whatever total has been printed under control of the accumulator AC—PT is entered into the accumulators AC—LT and AC—GT.

In this respect it is to be noted that totals so read out of the accumulator AC—PT are read into both the accumulators AC—LT and AC—GT, but if it were desired to enter such totals merely into either one or the other of the accumulators AC—LT or AC—GT, then the cam plate 757 associated with whichever accumulator was to receive the entries would be formed, in the manner above described, to bring only the gear segment 726 on the rocker 722 of this accumulator into mesh with teeth on the rack 727. The cam plate 757 for the other accumulator, in such circumstances, would merely have a prolonged dwell which would maintain the rocker 722 thereof in the intermediate position in which the rocker 722 is shown in Fig. 33. However, in the present instance I find it convenient to enter the totals read out from the accumulator AC—PT into both the accumulators AC—LT and AC—GT in the manner explained above.

In order to insure that the shaft 750 will remain in such position as to maintain the cam plates 757 in their proper positions in the course of a

total taking operation, the disc 754 carrying the teeth 753 and 756, that are engageable by the pawl 752, has teeth 978, 979 and 980 thereon. When the pawl 752 engages the tooth 753, which occurs when a total is to be printed under control of the accumulator AC—PT, the tooth 978 is moved into a position to be engaged by the shoulder 981 formed in a link 982 that is pivotally mounted, as indicated at 983 on a bracket as 984 that extends outwardly from the adjacent side frame member 505. The link 982 has a lug 985 at the lower end thereof that is engageable by a pin 986 on the cam shaft 560 near the end of a rotation thereof in each instance where the shoulder 981 has engaged a tooth as 978. It is this that is effective to disengage the shoulder 981 from whichever tooth it has engaged to thereby free the shaft 750 and the parts fast thereon to the effect of the spring 762 to thereby permit these parts to be returned to their normal at rest position determined by the adjustment screw 761 as aforesaid.

It is to be noted that in total taking operations certain control circuits for effecting this are regulated by switches included in a switch unit 987, Figs. 9, 49, 50 and 51, this arrangement being described in further detail hereinafter. However, when a ledger total as LT, Fig. 6, is to be printed on a proof sheet as PS₂, circuits are closed through the switching unit 987 and other devices are also operated under the control of this unit to enable this to be effected. In this regard the taking of a ledger total is under control of a tab as TBS, Fig. 4, that is provided on the last printing and control device in a series thereof related to the ledger or the like relative to which a total as LT is desired to be taken. It will be understood that a tab as TBS is provided on a printing and control device as D at a predetermined tab position thereon. Therefore, when a printing and control device bearing a tab as TBS attains station IV, Fig. 8, hereinabove described, this tab is effective to actuate a switch, generally indicated by 988, Fig. 18, through the intermediary of a rod 989 which is actuated by a pawl 990 mounted in the printing and control device guideway G in position to cooperate with a tab as TBS when a printing and control device bearing such a tab comes to rest in station IV. The circuit closed by the switch 988 is effective to set the cam shaft 991, Fig. 49, in the switch unit 987 in operation, and this cam causes the Bowden cable 992, Figs. 32B, 33, 49 and 51, to be pushed in such a way that the shroud 755, Fig. 32B, is moved from position above the tooth 756 to thereby disclose this tooth to the pawl 752.

Hence, when the solenoid 746 is thereafter energized to cause the pawl 752 to move toward the teeth 753 and 756, the pawl, in this instance, engages the tooth 756. This so rotates the shaft 750 that the cam plates 757 associated with the accumulators AC—PT and AC—GT move into positions to be effective to dispose the rockers as 722 therein in the intermediate positions thereof shown in Fig. 33. This is also effective to move the rockers 722 in the accumulator AC—LT into such position that the gear segment 726 thereon meshes with the rack 728. Consequently when, in the manner hereinabove described, the rack 728 is actuated by the cam 766, the accumulator wheels of the accumulator AC—LT are engaged with the racks 706 on the slide sections 555_f. Thereafter, in the manner described hereinabove with reference to the taking of a total from the accumulator AC—PT, the accumulator wheels

185 of the accumulator AC—LT are effective to set up type characters TC_f on the type segments TS2 in printing position so that a ledger total as LT, Fig. 6, may be printed on a proof sheet as PS2. It will be understood that in the course of this operation the pin 975, Fig. 32, on the rocker 122 of the accumulator AC—PT disposes the teeth on the associated plate 977 in position to engage thick teeth on the accumulator wheels 705 of the accumulator AC—PT, and therefore these accumulator wheels are restored to zero when a total is read out therefrom and printed on the proof sheet.

In this respect it is to be understood that the circuits in the timing or switching unit 981, Fig. 49, are such that the taking of a ledger total is suspended until after a page total as PTT has been printed on the proof sheet as PS2, Fig. 6, and in such an instance energization of the solenoid 146 to bring about printing of a page total PTT is effected under control of a switch included in the switch unit 981 for the reason that a page total is to be printed on the proof sheet when a ledger total is to be printed irrespective of whether or not twenty impressions have been made on the web since the last page total was printed. It will also be understood, as can be ascertained by reference to Fig. 6, that the page total PTT is printed prior to the time the ledger total LT is printed, for whatever amount is printed as a page total in this instance must be entered into the accumulator AC—LT in the manner hereinabove described prior to the time the ledger total is read out therefrom.

When a grand total as GT is to be printed on a proof sheet as PS3, Fig. 7, this is effected under control of the accumulator AC—GT and the present machine is arranged to enable the printing of such a total to be effected manually. Therefore, a crank 993, Fig. 25, is provided at the forward end of the shaft 750 which will be disposed in a position convenient to the front of the machine. When this crank is grasped and the shaft 750 is rotated it is moved into such a position that the shoulder 981, Fig. 33, seats in the tooth 980, 45 it being understood that this shoulder seats on the tooth 979 when a ledger total is to be taken. Engagement of the shoulder 981 with the tooth 980 causes the cam shaft 750 to assume such a position that the cam plates as 757 are located in such position that they are effective to dispose the rockers as 122 in the accumulators AC—PT and AC—LT in the intermediate position in which the rocker 122 is shown in Fig. 33. This, however, is also effective to dispose the rocker 122 in the accumulator AC—GT in such position as to have the gear segment 726 thereon meshed with the rack 728. This also causes the teeth of the comb 977 in this accumulator to be disposed in position to effect zeroing of the accumulator wheels 705 in the accumulator AC—GT when the total accumulated therein is read out therefrom to enable setting up of the type characters TC_f on the type segments TS2 to thereby enable the platen PP to print a grand total as GT on a proof sheet as PS3. When a grand total is to be printed under control of the accumulator AC—GT, not only is the shaft 750 manually rotated, as above described, but further, as will be described more fully hereinafter, the cam shaft 560 is set in operation manually by the manual closing of a switch which will be described.

It is to be understood that whenever a ledger total as LT and a grand total as GT are printed on the web W, it is either necessary or best to 70

insure that the counting device included in the pager and proofer mechanism PM is restored to a zero position so as to thereby insure that this device will be effective to count the printing of twenty items on the succeeding proof page so as to insure that a page total as PTT will be printed on the web W after the last of such twenty items. Hence, as explained, means are provided in the pager and proofer mechanism PM to enable the aforesaid counting mechanism to be manually zeroized when desired.

ELECTRICAL CONNECTIONS AND OPERATION OF THE MACHINE

When the machine is to be set in operation the plurality of printing and control devices D are removed from a drawer J and by arranging the drawer over the magazine H, which is rocked to a position convenient to have the printing and control devices dumped from the drawer thereunto, this may be expeditiously effected. Thereafter the magazine is arranged in vertical position so that the lowermost printing and control device in the stack thus introduced into the magazine is disposed at station I, Fig. 8.

Furthermore, a roll of paper R, Fig. 1, of a width equal to that desired of the proof sheets as PS1, Fig. 5, is mounted on the web support WS, Fig. 1, at the front of the machine. The web W is then withdrawn from this roll and is threaded through the feeding devices therefor in the pager and proofer mechanism PM pass the knife 945, Fig. 52, so that in the course of operation of the machine after twenty items, in the present instance, have been printed on the web W it may be divided into proof sheets as PS1, Fig. 5.

Additionally, a pack of blank checks as S, Fig. 3, is disposed on end on the platform 86, Fig. 1, of the sheet feeding mechanism SR and the follower device SF is disposed to force these sheets toward the sheet withdrawing means included in the sheet feeder SR.

First preliminary cycle

With the machine thus equipped with the sheets and web on which it is to operate and with a supply of devices therein from and under control of which it is to operate, the driving motors for the machine are set in operation so that the machine will be in condition to operate under controls provided therein, as will be explained presently. To this end the main switch 1000, Figs. 1, 2 and 57, is closed to thereupon close circuit from line wires 1001 and 1002 to the conductors 1003 and 1004 which lead to the terminals of the main drive motor 95 and to the terminals of the motor 95PM of the pager and proofer mechanism PM which thereupon are set in operation and thereby the main drive shaft 90 is set in operation.

Moreover, I find it advantageous to operate many of the controls included in the machine from a source of direct current and since this may not always be available in places whereat the machine of the present invention is to be used I mount a direct current generator DCG, Figs. 9 and 57, on a suitable bracket on the main frame F, an endless belt 1005, Fig. 9, being passed about pulleys 1006 and 1007 respectively provided on the shaft of the main drive motor 95 and the drive shaft of the generator DCG.

In order to simplify the wiring diagram, Figs. 54 to 57, inclusive, I have shown batteries B at various positions therein to indicate a source of

direct current and it is to be understood that each of these batteries B and the ground shown in association therewith as well as other indications of grounds represents conductors leading from the generator DCG, this convention avoiding extending conductors from this generator throughout the aforesaid wiring diagram, the generator DCG being connected to a grounded battery MB to indicate that each battery B and a conventionally indicated ground are related to the generator DCG.

Thus, with a source of power available to drive various operative mechanisms in the machine and with the sheets and web arranged in the machine in condition to be operated upon and with a supply of printing and control devices in the magazine H, the machine may be set in operation to produce checks as S and proof sheets as PSI. To initiate this, the switch 1008, Figs. 2 and 54, is closed to close circuit from the conductor 1009, which leads from the battery B1, that is grounded as indicated at 1010, through the blade 1011 of the switch 1008 to the blade 1012 thereof and thereupon through the conductor 1013 to the terminal strip 1014, Fig. 55. A conductor 1015 leads from the terminal strip 1014 to one end of the winding of the solenoid 170, Figs. 55 and 10, a conductor 1016 leading from the other end of the winding of the solenoid 170 through a closed switch 1017 to ground at 1018 and thereupon the solenoid 170 is energized. The switch 1017 may be manually opened to prevent unauthorized operation of the machine. It is to be noted that closure of the switch 1008 does affect the conductors shown in Fig. 55 leading from the terminal strip 1014 since these are extended to switches which are open at this time so that no circuit is closed therethrough.

Energization of the solenoid 170, Fig. 10, as aforesaid brings about engagement of the normally separated parts of the clutch 120 and therefore since the main drive shaft 90 is in operation at this time such engagement of the separable portions of the clutch 120 causes the shaft 117 to make a complete revolution, as explained hereinabove. This is effective in this particular operation of the machine to advance the first printing and control device in the series thereof, which devices will have been introduced into the magazine, from station I to station II, Fig. 8, and in this particular operation certain other operative functions are effected.

Thus, as will be explained presently, in each cycle of operation of the machine in which the shaft 117, Fig. 10, is set in operation, the Bowden cables 357, Fig. 20, are pushed and consequently immediately after the shaft 117 is set in operation, the solenoid 472, Fig. 37A, which is operative to effect restoration of the Bowden cables 357, is energized, and this is effected under control of one of the switches 1019, Figs. 5 and 10, that include discs as 1020 that are connected to the shaft 117 for operation therewith. In the present instance the disc 1020a carries a contact strip which extends circumferentially thereon for a distance sufficient to close circuit between the blades 1021 and 1022 of this particular switch 1019. A conductor 1023, Fig. 55, leads from the battery B2 to the switch blade 1021 and when circuit is closed between the switch blades 1021 and 1022, circuit is extended through the conductor 1024, Figs. 55 and 54, to the switch blade 1025, Figs. 41 and 54, that is associated with a switch disc 1026k that includes a contact strip which at this time is disposed between the blade 75 associated with the disc 1020b on the shaft 117.

1025 and the blade 1027 for at this time the shaft 802 is stationary, this shaft being set in operation at a time and in a manner described hereinafter. Therefore, circuit is extended from the switch blade 1027 through the conductor 1028, Figs. 54 and 56, to one end of the winding of a solenoid 472, Figs. 37A and 57, and this circuit is completed to ground at 1031 through the conductors 1032 and 1033 which results in energization of the solenoid and causes the bifurcated arm 466, Fig. 37A, to act on the restoring plates 441 to thereupon restore the Bowden cables 357 to their normal at rest position.

In the course of rotation of the shaft 117, the 15 conjugated cams 406 and 407, Fig. 12, will, in the manner described hereinafter, cause the sensing head 352, Fig. 20, to move toward station II. In this cycle of operation this occurs at the time when no printing and control device is disposed in this station. Therefore pins 351 20 push each Bowden cable as 357 to thereby dispose all of the pins as 442, Fig. 37A, in a position in which they would cooperate with the steps PS on the positioning templets PT, Fig. 37B, if the multiplying mechanism M were to be set in 25 operation in this cycle of operation, but this is not done in this first preliminary cycle. Likewise, a selector pin as 426 will move toward station II but because no printing and control device is disposed in station II at this time the movement of this pin will be ineffective on the switches in 30 the switch pile 435, Fig. 19. Subsequent to the time the sensing pins 351 and 426 thus move toward station II, the conjugated cams 406 and 407, Fig. 12, will elevate the sensing head 352 into its normal at rest position and after this position is attained the carrier bars 121 and 122 will be effective to dispose the first printing and control device in the series thereof in the machine 35 in station II.

It is essential in machines of the character to which the present invention pertains that the presence or absence of printing and control devices in the magazine H be ascertained in each 40 cycle of operation and if a printing and control device is not disposed in station I, operation of the machine is to be interrupted.

To this end in the present instance a relay 1034, Figs. 15, 20 and 57, is mounted adjacent 50 to station I and a pin 1035, Fig. 57, is engaged with the movable contact 1036 of this relay. If a printing and control device is disposed at station I, the pin 1035 moves into engagement therewith and prevents the contact 1036 from engaging the 55 stationary contact 1037 of the relay 1034 so as to prevent closure of circuit through these contacts. If, however, no printing and control device is disposed at station I, then the contact 1036 will engage the contact 1037 and extend circuit through conductor 1035' from battery B22 to terminal strip 1430, Fig. 56, to effect energization of relay 1195, Fig. 56, for a purpose explained hereinafter.

However, in order to effect a detecting operation 60 to determine whether or not a printing and control device is disposed in station I in this first cycle of operation, and in every other cycle of operation, the relay 1034 is energized in every cycle of operation in which the shaft 117, Fig. 10, is set in operation. Therefore, one end of the winding of the relay 1034 is connected to ground, as indicated at 1038. A conductor 1039, Figs. 57 and 55, leads from the other end of the winding of this relay to the blade 1040, Figs. 55 and 10, 70 associated with the disc 1020b on the shaft 117.

Therefore, in the course of rotation of the shaft 117 a contact strip on this disc closes circuit from a switch blade 1040 to the switch blade 1041 which, through a conductor 1042, is connected to battery B3, Fig. 55, and it is this that brings about energization of the relay 1034 for the purpose described hereinabove.

It is also essential to proper automatic operation of the present machine that a printing and control device be disposed in station II and therefore means for detecting the presence or absence of a printing and control device at this station are provided. This means is also effective in the event a printing and control device moved to station II is not accurately located thereon for if a printing and control device is not accurately positioned in, or is not moved to, station II, operation of the machine is to be interrupted at the end of the cycle of operation in which this condition occurs. Therefore, the pawl 239s, Figs. 15 and 16, which, like the pawls 239, is adapted for cooperation with the notch 238, Fig. 4, in a printing and control device, is arranged to control electrical circuits in the event the nose 240s on this pawl does not seat in a notch 238 in a printing and control device at station II, which indicates that a printing and control device has not reached this station or is not properly positioned therein, the pawl 239s also being effective to open an electrical circuit when a printing and control device is disposed at station II is in such position that the nose 240s seats in the notch 238 therein.

Therefore, as best shown in Fig. 16, the pawl 239s has an extension 1043 thereon which carries a fibrous plate 1044 in which a blade 1045 of a switch, generally indicated by 1046, Figs. 16 and 55, is disposed. Whenever a printing and control device is properly disposed in station II and the nose 240s moves into the notch 238 therein, a contact on the blade 1045 is moved from engagement with a contact on the blade 1047 of the switch 1046 to thereby open an electrical circuit as will be explained.

Assuming, therefore, that in the present instance the printing and control device which is advanced from station I to station II comes to rest accurately in station II, the nose 240s will enter the notch 238 therein and disengage the contacts on the blades 1045 and 1047, and this so conditions an electrical circuit that when, at a predetermined time in the cycle of operation of the machine, circuit is extended to the switch blade 1047, the circuit will not be extended beyond the switch 1046.

In order that circuit will be extended to the switch blade 1047 at the time in a cycle of operation of the machine at which a printing and control device should be properly disposed at station II, a switch disc 1020c, Fig. 55, is included in the group of discs 1020 connected to the shaft 117 and a blade 1048 associated with this switch disc is connected through the conductor 1023 to the battery B2. A conductor 1049, Fig. 55, leads from the other blade 1050 of this switch to the switch blade 1047.

In event a printing and control device does not move into station II, the nose 240s moves inwardly in an amount substantially greater than that in which it moves when this nose seats in a notch 238 in a printing and control device D. In this event the extension 1043 on the pawl 239s is so moved that the blade 1045 is moved into engagement with the blade 1047. Therefore, when circuit is extended to the switch blade 1047,

as aforesaid, this circuit may be extended on through the switch blade 1045, conductor 1051, Figs. 55 and 57, to one end of the winding of the relay 1052, the other end of the winding of this relay being connected through a conductor 1053 to ground at 1054. Thereupon the relay 1052 is energized to latch the movable contacts 1055 and 1056 thereof in such position that the contact 1056 will be disengaged from the stationary contact 1058 and also so that the contact 1055 is engaged with the contact 1057, for a purpose explained hereinafter. Since the relay 1052 is of the mechanically latching type, when this relay is so energized, for example, in the manner just described, the contacts 1055 and 1056 are mechanically latched and retained in their latched positions just described. The manner in which the 1055 and 1056 contacts are unlatched is described hereinafter.

Moreover, if a printing and control device is disposed in station II in such position that the nose 240s cannot move into the notch 238 therein, then the pawl 239s is disposed in such position that the extension 1043 thereof moves the blade 1045 into engagement with the blade 1059 included in the switch 1046. By referring to Fig. 55 it will be seen that the blade 1059 is connected by a conductor 1060 to the conductor 1049. Therefore, engagement of the switch blade 1045 with the contact 1059 results in energization of the relay 1052 when the switch disc 1020c, Fig. 55, is effective at the aforesaid time in the operation of the machine to close circuit between the blades 1048 and 1050 associated therewith.

With respect to the foregoing safety arrangement for determining whether or not a printing and control device is disposed in station II, it will be manifest that the switch disc 1020c could be arranged to close circuit between the blades 1048 and 1050 associated therewith at any time in the cycle of operation subsequent to the time when a printing and control device should have been advanced to and accurately been disposed in station II. However, I have found it advantageous to so arrange the switch disc 1020c that it closes circuit between the blades 1048 and 1050 associated therewith at the very end of a cycle of a rotation of the shaft 117 for I have found this to be an advantageous time at which to mechanically latch the contacts 1055 and 1056, Fig. 58, in the latched positions thereof described.

It will be noted in connection with the foregoing that the disc 1020c is disposed in position to close circuit to the relay 1052 and latch up the contacts thereof whenever the shaft 117 is in its at rest position. Therefore, as in the present instance, when a supply of printing and control devices is initially introduced into the machine, there will not be a printing and control device at station II at the time when the button 1008 is initially pressed to advance the printing and control devices to printing position. Hence, when there is no printing and control device at station II and the generator DCG is initially set in operation (this generator being indicated by the battery B2 in the circuit for the relay 1052), the relay 1052 is energized and this latches up the contacts thereof to open the circuit normally established therethrough. It is, however, advantageous to unlatch the contacts of the relay 1052 in every cycle of operation of the machine, but in this respect it is to be noted that in the automatic operation of the machine described hereinafter a succeeding cycle of operation cannot be initiated after a cycle of operation in

which a printing and control device has failed to come to proper position in station II, because the circuit through which an automatic cycle of operation is initiated is established through the contacts 1055 and 1057, Fig. 57, of the relay 1052 which will be latched in disengaged position at the end of a cycle of operation in which a printing and control device fails to come to rest at station II.

In the preliminary cycles of operations, however, which are, for example, initiated by closure of the switch 1008, as is this first preliminary cycle of operation, the relay 1052 is ineffective to open the energizing circuit that is closed by closure of the switch 1008. Therefore, even though when the machine is initially set in operation, the relay 1052 is energized so as to latch the contacts thereof in the aforesaid positions, these contacts are unlatched in the succeeding cycle of operation which is also initiated by closing the switch 1008. To this end an unlatching relay 1152 is associated with the contacts of the relay 1052. Energization of this relay is controlled from the shaft 117 which, as stated, is set in operation when the switch 1008 is closed. Energization of this unlatching relay 1152 is effective to unlatch the contacts of the relay 1052 in the event they are locked up. It is to be noted, however, that the relay 1152 will be ineffective for this purpose in the course of automatic operation of the machine for the reason that if the relay 1052 is energized in an automatic cycle of operation of the machine a succeeding cycle will not be initiated and the shaft 117 will not be rotated and the unlatching relay 1152 will not be energized.

However, in some instances where the last printing and control device, in a series thereof moving through the machine, has reached station II, the last printing and control device will move from station II to station III in one cycle of operation and will be moved from station III to V in a succeeding cycle of operation. It is advantageous, in such circumstances, to effect unlatching of the contacts of the relay 1052 by energization of the relay 1152.

Therefore, a circuit for energizing the relay 1152 is established through a switch disc 1020f, Fig. 55, included in the switch discs 1020 on the shaft 117. This switch disc 1020f carries a contact strip which closes circuit between the blades 1153 and 1154, Fig. 55, very shortly after rotation of the shaft 117 is initiated. Thereupon circuit is extended from battery B2, Fig. 55, and conductor 1023 through blade 1153, the contact strip on the disc 1020f, blade 1154, conductor 1155, Figs. 55 and 57, to one end of the winding of the relay 1152 and thence to ground through the conductor 1156. This is effective to energize the relay 1152 and effect unlatching of the contacts of the relay 1052 which thereupon assume their normal condition, shown in Fig. 57, to be moved to their latched condition only after a printing and control device does not attain station II in this cycle of operation, in which event, near the end of this cycle of operation the relay 1052 will be energized.

Second preliminary cycle

Closure of the switch 1008 to effect the advancement of the first printing and control device in the series thereof from station I to station II need only be sufficiently prolonged to initiate the cycle of operation in which this is effected. However, in order to condition the machine for fully auto-

matic operation, it is necessary to effect another cycle of operation much like that described hereinabove and, therefore, after the completion of such a cycle of operation, the switch 1008 is again closed to again effect energization of the solenoid 170 to again engage the clutch 120 and again cause the shaft 117 to make a full revolution. When this is done the operations, hereinabove described, are repeated and in this instance the first printing and control device is advanced from station II to station III and the second printing and control device is advanced from station I to station II.

However, shortly after the carrier bars 121 and 122 start to move rearwardly upon such second closure of the switch 1008, the solenoid 472, Figs. 37A and 57, is again energized in the manner hereinabove described and since in the preceding cycle of operation all of the Bowden cables as 357 were pushed, all of these Bowden cables in this instance are returned to their normal at rest position. Thereafter and still while the carrier bars 121 and 122 are moving rearwardly, the conjugated cams 406 and 407, Fig. 12, cause the detector head 352 to move downwardly and in this instance only those pins 351 which pass through perforations as 85 in the first printing and control device still in station II at this time are effective to push Bowden cables as 357. This is effective to dispose pins 442, Fig. 37A, in digit representing positions corresponding to digits represented by the perforations 85 in the printing and control device at station II. These pins remain in this position to cooperate with steps PS on the positioning templets PT in the early part of the succeeding cycle of operation, at which time the multiplying mechanism M is set in operation for the first time. It will be understood that the aforesaid energization of the solenoid 472 to effect restoration of the Bowden cables as 357, and therefore the pins 442, occurs after the steps as PS have cooperated with those pins 442 which are in digit representing positions in the course of an operation of the multiplying mechanism M.

If the first printing and control device disposed at station II is not equipped with a tab as TB, when the detector head 352 is moved theretoward, as aforesaid, a pin as 426, Fig. 20, is not effective to actuate the switches included in the switch pile 435, Figs. 19 and 57. In such circumstances, the machine is conditioned to make impressions from the printing and control device in the succeeding cycle of operation of the machine when this printing and control device reaches stations III and V.

When the switches in the switch pile 435 are not operated under the effect of a sensing pin as 426, circuit is not extended to the switches in this pile until a predetermined time in the operation of the machine which is subsequent to the time at which the detector head 352 is lowered. For this purpose, still another switch disc 1020d is provided in the group of switch discs 1020 connected to the shaft 117 and blades 1061 and 1062 are arranged to cooperate with a contact strip included on this switch disc.

The blade 1062, Fig. 55, is connected by conductor 1023 to the battery B2 and a conductor 1063, Figs. 55 and 57, leads from the switch blade 1061 to a switch blade 1064, Figs. 57 and 19, in the switch pile 435. A contact on this switch blade is normally spaced from a contact on the cooperating switch blade 1065 and is not engaged therewith unless a sensing pin as 426 engages a tab as TB on a printing and control device dis-

101

posed at station II. It will be noted that a conductor 1066 leads from the conductor 1063 to a switch blade 1067 in the switch pile 435 which has a contact thereon that is normally engaged with a contact on the switch blade 1068. Therefore, when circuit is extended through the conductors 1063 and 1066, this circuit is extended through the blades 1067 and 1068 to the conductor 1069 which leads to a switch 1070 which, in a circumstance where all printing and control devices not equipped with tabs as TB are to be printed, is closed. A conductor 1071 leads from the switch 1070 to a terminal 1072 of a switch 1073 which, while closed in the present instance, is ineffective since the conductor 1074 leading therefrom leads to a switch 1075 which is open in the present instance where all printing and control devices not equipped with tabs as TB are to have impressions made therefrom. A conductor 1076 leads from the terminal 1077 of a switch 1078 which is also open in this instance.

In this respect it is to be noted that the switches 1070, 1075, 1073 and 1078 are so arranged that when these switches are disposed in other than those positions in which they are shown in Fig. 57, the circuits may be so arranged that only those printing and control devices bearing tabs as TB will have impressions made therefrom, or these switches may be disposed in still another position wherein all printing and control devices passed through the machine will have impressions made therefrom irrespective of whether or not these printing and control devices are equipped with tabs as TB. The purposes for which this is effected are well understood in the art, but, as explained above, in the present instance, the aforesaid switches are arranged so that all printing and control devices which do not bear tabs as TB are to have impressions made therefrom.

A conductor 1079, Figs. 7 and 56, leads from the terminal 1077 to one end of the winding of a relay 1080 and a conductor 1081 leads from the other end of this winding to a terminal 1082 and thence to ground through a conductor 1083.

Therefore, whenever a sensing pin as 426 does not engage a tab as TB on a printing and control device D disposed at station II, circuit is closed from battery B2, Fig. 55, through conductor 1023, switch blade 1062, contact strip on disc 1020d, blade 1061, conductor 1063, Figs. 7 and 57, conductor 1066, blade 1067, blade 1068, conductor 1069, closed switch 1070, conductor 1071, terminal 1072, conductor 1076, terminal 1077, conductor 1079 and the winding of relay 1080 to ground through conductors 1081 and 1083 and thereupon the relay 1080 energizes. Such energization of the relay 1080 engages the movable contact 1085 thereof with the stationary contact 1087 thereof and disengages the movable contact 1084 thereof from the stationary contact 1086 thereof. This conditions a circuit through which circuit is closed to the solenoid 831, Figs. 41, 42 and 54, of the main clutch MC, in a manner and for a purpose described presently and which is effective to set the shaft 802 of the switches 800 in operation in an automatic cycle of operation of the machine. The relay 1080 is also of the mechanical locking type and is also arranged to be electrically released in every cycle of operation of the machine. The timing is such that circuit is closed to the means for securing unlatching or releasing of the relay 1080 prior to the time circuit is closed thereto in a particular cycle of operation of the machine to effect energization thereof in the

102

manner above described when this is to be done.

To this end another switch disc 1020e, Fig. 55, is included in the group of switch discs 1020 connected to the shaft 117, and blades 1088 and 1089 are disposed to be engaged by a contact strip on this switch disc. The contact strip on this switch disc closes circuit between the blades 1088 and 1089 prior to the time the contact strip on the switch disc 1020d closes circuit between the blades 1061 and 1062 associated therewith for a purpose explained presently.

When the contact strip on the disc 1020e closes circuit between the blades 1088 and 1089 circuit is extended from the battery B2 and conductor 1023 to conductor 1090, Figs. 55, 57 and 56, to one end of the winding of the release relay 1091 for the mechanical locking relay 1080, the other end of the winding of this relay 1091 being connected to ground through conductors 1092 and 1083. Therefore the extension of circuit to the release relay 1091, in the manner just described, is effective to bring about unlatching of the contacts 1084 and 1085 of the relay 1080 with respect to the contacts 1086 and 1087 thereof in the event these contacts had been latched by reason of energization of the relay 1080 in a previous cycle of operation. This unlatching operation is effected irrespective of whether or not the relay 1080 has been energized to latch the contacts thereof as aforesaid.

Third preliminary cycle

After two preliminary cycles of operation of the machine have been effected, as above described, by successive closures of the switch 1083, Fig. 54, the first printing and control device in the series thereof passing through the machine is disposed at station III and the second printing and control device in the series is disposed at station II. Moreover, at this time, as explained above, pins 442, Fig. 37A, are disposed in the position in which they may cooperate with the steps PS on positioning templets PT of the templet-gangs TG in the multiplying mechanism M. With the parts thus arranged the first sheet S is to be released in the succeeding cycle of operation so that the changeable data A and the variable data V1 and V2 may be printed thereon at the proper positions. Moreover that portion of the web W which is to constitute the top of the first proof sheet as PS1 is disposed in position to receive an impression from the type segments TS2.

With the machine thus arranged, the switch 1095, Figs. 2 and 54, is manually closed to engage the contacts on the blades 1096 and 1097 thereof to thereby effect energization of the relay 1098, Fig. 54. This is effected by the extension of circuit from the battery B1, Fig. 54, through conductor 1009 to the blade 1096 and thence through blade 1097, conductor 1099 to terminal 1103 and thence through conductor 1101 to one end of the winding of the relay 1098. Circuit is extended from the other end of this winding through conductor 1102 to the terminal 1103 and thence through conductor 1104 to terminal 1105 and to ground through conductor 1106. Hence, upon closure of switch 1095 the relay 1098 is energized.

In order to indicate that the relay 1098 has been energized so as to indicate that operation of the machine is progressing through a third preliminary cycle, a signal lamp 1107, Figs. 1 and 56, is rendered operative and, as can best be ascertained by reference to Fig. 1, this lamp is located to be in plain view of the operator. Circuit is extended to this lamp 1107 to render it

operative through a conductor 1108, Figs. 54 and 56, from the terminal 1100, Fig. 54, to one terminal of the lamp 1107 to ground at 1110. Since circuit is extended to terminal 1100 only when the relay 1098, Fig. 54, is to be energized, the lamp 1107 will be rendered operative only during this third preliminary cycle, which is the only time the relay 1098 is energized.

Inasmuch as it is preferable that the switch 1095 be closed only normally and to avoid the necessity of holding this switch closed throughout this third preliminary cycle, a stick circuit is provided for holding the relay 1098 energized once it is energized in the manner above described. To this end a pair of contacts 1111 and 1112, Fig. 54, is provided on the relay 1098 which contacts are engaged as soon as this relay is energized. The stick circuit that is thus established upon engagement of the contacts 1111 and 1112 is closed through a switch including one of the switch discs 1026 mounted on the shaft 802, Figs. 41 and 54. It is the disc 1026a in this group of switch discs that is effective to close this stick circuit for at the time this stick circuit is to be closed, the contact strip on this disc will be closing circuit between the blades 1113 and 1114 associated therewith.

The source of current in this instance is afforded by the battery B4, Fig. 54, and circuit is extended from this battery through the conductor 1115, terminal 1116, thence through conductor 1117, terminal 1118, conductor 1119 to the blade 1113 and thence through the contact strip on the disc 1026a, blade 1114, conductor 1120, to contact 1112, and thereafter through contact 1111 through conductor 1121 to terminal 1122 and thence through conductor 1123 to the end of the winding of the relay 1098 to which the conductor 1101 extends. This is also effective through the conductor 1101 to extend circuit to the terminal 1100 so as to thereby also maintain the lamp 1107 operative.

The stick circuit thus established for the relay 1098 remains effective until near the end of the third preliminary cycle at which time the contact strip on the disc 1026a breaks the circuit between the blades 1113 and 1114 to thereupon enable the relay 1098 to deenergize. Moreover, while the contact strip on the disc 1026a will interconnect the blades 1113 and 1114 in every rotation of the shaft 802, this will be ineffective to close circuit to the winding of the relay 1098 in all instances save those wherein energization of this relay has been initially effected by closure of the switch 1095 for the reason that the circuit that is closed through the blades 1113 and 1114 associated with the disc 1026a cannot be established unless the contacts 1111 and 1112 of the relay 1098 are engaged, and this is only effected when the relay 1098 is energized upon manual closure of the switch 1095.

By reference to Fig. 54, it will be seen that the relay 1098 includes, in addition to the contacts 1111 and 1112, sets of contacts 1126 and 1127, 1128 and 1129, 1130 and 1131, and 1132 and 1133. So long as the relay 1098 is deenergized, the contacts 1111 and 1112 are disengaged to open the stick circuit that is established through engagement thereof, but the remaining contacts of this relay are normally engaged to normally establish the circuits that are extended therethrough. However, in this third preliminary cycle of operation, these normally closed contacts are disengaged for reasons that will be made apparent presently.

After the relay 1098 has been initially energized and the stick circuit therefor described above has been established, the operation of the machine in this third preliminary cycle is initiated by depressing the center button 1137 of the start-stop switch 1135, Figs. 2 and 54. By reference to Fig. 54 it will be seen that the start-stop switch 1135 is of the character embodying an outer shell 1136 in which the manually depressible start button 1137 is mounted. As will be explained hereinafter, depression of the shell as 1136 is effective to interrupt automatic operation of the machine. Depression of the start button 1137 engages contacts on the blades 1138 and 1139 to close the starting and main control circuit to be described hereinafter.

In this respect it is to be noted that when a supply of printing and control devices is introduced into the magazine H, it is essential that one or the other of the drawers J, Fig. 1, be disposed in the upper or printing and control device receiving position thereof. In order to insure that this condition will prevail, a pair of switches 1140 and 1140a, Fig. 56, is provided. Each of 20 these switches includes a pair of blades as 1141 and 1142, and 1141a and 1142a, and also other pairs of blades 1143 and 1144, and 1143a and 1144a. Inasmuch as disposition of either one of the drawers J in its upper printing and control 25 device receiving position is to be effective to enable the aforesaid starting circuit to be established, the blades 1141 and 1142 of the switch 1140 are connected in parallel with the blades 1141a and 1142a of the switch 1140a. To this 30 end a conductor 1145 interconnects the blades 1141 and 1141a through a terminal 1146, and a conductor 1147 interconnects the blades 1142 and 1142a through a conductor 1148 that has a terminal 1149 therein. Thus so long as either the 35 blades 1141 and 1142 or 1141a and 1142a are engaged, circuit will be established to the terminals 1146 and 1149. Consequently, when either one of the drawers J is in its upper printing and control device receiving position, circuit 40 is established to the terminals 1146 and 1149.

The aforesaid starting circuit which is closed upon depression of the button 1137, Fig. 54, extends from battery B5, Fig. 56, through conductor 1150 to terminal 1149 and thence through which 45 ever one of the switches including the blades 1141 and 1142 or 1141a and 1142a circuit is extended to the terminal 1146. Circuit continues from terminal 1146 through conductor 1151, Figs. 56 and 57, to contact 1055 of relay 1052. Assuming that 50 in the preceding cycle of operation of the machine a printing and control device was properly disposed in station II, the relay 1052 will not have been energized and in such circumstances the contact 1055 will be unlatched and therefore engaging the contact 1057. Consequently, circuit 55 will be extended from contact 1057 through conductor 1157, Fig. 57, to a terminal 1158 and thence through conductor 1159, Figs. 57 and 54, to blade 1160 associated with switch disc 1026b, Fig. 54, 60 which also has a blade 1161 associated therewith.

At this time the shaft 802 is at rest and consequently a contact strip on the switch disc 1026b is not closing circuit between the blades 1160 and 1161. Therefore circuit is not extended from the 65 blade 1161 through conductor 1162, Figs. 54 and 56, to terminal strip 1163. However, another conductor 1164, Figs. 57 and 55, leads from the terminal 1158, Fig. 57, to a blade 1165, Fig. 55, associated with a switch disc 1166a in the set of switch discs 1166 connected to the main shaft 499, Fig. 75

34, of the multiplying mechanism M. At this time a contact strip on the disc 1166a is closing circuit between the blades 1165 and 1183 associated therewith and therefore circuit is further extended through the conductor 1167, Figs. 55, 57 and 56, to the aforesaid terminal block 1163. Thus even though circuit was not extended to the terminal block 1163 under control of the switch disc 1026b, circuit is extended to this terminal block under control of the switch 1166a.

From the terminal block 1163 circuit is extended through a conductor 1168 to a contact 1169, Fig. 56, of the relay 1170 that is only energized when a ledger total is to be taken, wherefore at this time this relay is deenergized and consequently the contact 1169 thereof is engaged with the contact 1171. Therefore, circuit is extended from the contact 1171 through a conductor 1176 to a terminal 1177, and thence through conductor 1178, Figs. 56 and 54, to the blade 1179 of the start-switch 1135, which switch also includes a blade 1181 which, when the shell 1136 of the start-stop switch is pushed downwardly, is disengaged from the blade 1179 to thereby break the starting circuit. However, until the shell 1136 is pushed downwardly, contacts on the blades 1179 and 1181 are in engagement. A conductor 1182 interconnects the blade 1181 with the blade 1138 of the starting switch. A conductor 1184, Figs. 54 and 56, leads from the blade 1139 to a terminal 1185, Fig. 56, and thence through conductor 1186 to terminal 1187. Conductor 1188 leads from the terminal 1187 to one end of the winding of a relay 1190, the other end of which is connected to ground through the conductor 1189.

Therefore, when the button 1137, Fig. 54, is pushed downwardly to engage contacts on the blades 1138 and 1139, the starting and main control circuit is closed from battery B5, Fig. 56, through conductor 1150 to terminal 1149 through whichever one of the switches 1140 or 1141 is closed to terminal 1146 and thence through conductor 1151, Figs. 56 and 57, to contact 1055 now engaged with contact 1057, and thereafter through conductor 1157, conductor 1164, Figs. 57 and 55, blade 1165, contact disc on disc 1166a, blade 1183, conductor 1167, Figs. 55, 57 and 56 to terminal block 1163, Fig. 56. The circuit is continued from the terminal block 1163 through conductor 1168, contact 1169, contact 1171, conductor 1176, terminal 1177, conductor 1178, Figs. 56 and 54, blade 1179, blade 1181, conductor 1182, blade 1138, blade 1139, conductor 1184, Figs. 54 and 56, terminal 1185, conductor 1186, terminal 1187, conductor 1188, through the winding of the relay 1190 to ground through conductor 1189. Thereupon the start and main control relay 1190 is energized.

In order to maintain the relay 1190 energized when circuit is closed thereto in the foregoing manner, and after the button 1137, Fig. 54, is released, a stick circuit is established for this relay upon energization thereof, and to this end a pair of normally open contacts 1191 and 1192, Fig. 56, are provided on this relay which are closed upon energization thereof, and it is this that closes the stick circuit for this relay 1190.

The stick circuit thus established is extended from the blade 1179, Fig. 54, of the start-stop switch 1135 to which blade circuit is extended from the battery B5, Fig. 56, in the manner explained above. In this instance the circuit leads from the blade 1179, now engaged with blade 1181, through blade 1181, and conductor 1182 to terminal 1182', and then through conductor 1193, Figs. 54 and 56, to the contact 1194 of the relay

1195, which is a normally deenergized relay and wherein the contact 1195 thereof is normally engaged with the contact 1196 thereof. Hence, since at this time the relay 1195 is deenergized, circuit is continued from the contact 1196 through the conductor 1197 to the contact 1192 which, when this stick circuit is to be established, is engaged with the contact 1191 and therefore circuit is continued through the conductor 1198 to the terminal 1187 and thence through conductor 1188, the winding of the relay 1190, to ground at 1189.

The relay 1195 constitutes a stop relay and through circuits described hereinafter is energized in the event of improper operation of the machine but other than this, once the stick circuit for the relay 1190, above described, is established, the relay 1195 remains deenergized and the contacts 1194 and 1196 remain engaged and the machine continues in automatic operation until the relay 1195, or one of the switches included in the stick circuit for the relay 1190 is opened as, for example, if the relay 1052, Fig. 57, is energized in the event a printing and control device does not move into proper position in station II, as explained hereinabove. It will also be understood that at any time it is desired to manually interrupt operation of the machine, the shell 1136 of the start-stop switch 1135, Fig. 54, may be pressed to thereby disengage the blade 1181 from the blade 1179. So to do breaks the stick circuit for the relay 1190. However, until this stick circuit is broken, the machine remains in normal automatic operation.

Upon energization of the relay 1190, Fig. 56, to effect normal automatic operation of the machine, the contacts 1200 and 1201 thereof are engaged and maintained engaged until this relay is deenergized. The contacts 1200 and 1201 are effective to close circuit to the solenoid 831, Figs. 54, 41 and 42, to thereupon effect engagement of the clutch MC, Figs. 41 and 42, which, as explained hereinabove, is effective to set the main switch shaft 802 in operation. The shaft 802, as has been explained, includes the switch discs 1026 which afford the main control for the machine in the automatic operation thereof. Consequently the energization of the solenoid 831 is effective to set in operation the main control of the machine.

The aforesaid circuit to the solenoid 831 is closed from battery B4, Fig. 54, through conductor 1115, terminal 1116, conductor 1117 to the blade 1202 associated with the switch disc 1026c, Figs. 54 and 41, which switch disc also has a blade 1203 associated therewith. At the time circuit is to be closed to the solenoid 831 the shaft 802 will, of course, be at rest and therefore a contact strip on the switch disc 1026c is closing circuit between the blades 1202 and 1203. Therefore the circuit extended to the blade 1202 is continued from the blade 1203 through a conductor 1204, Figs. 54 and 56, to the terminal 1205 and thence through conductor 1206 to the contact 1200 which, as stated, at this time is engaging the contact 1201. The circuit therefore continues through conductor 1207, Fig. 56, to the contact 1085 of the relay 1080, Fig. 56, which relay at this time is energized and therefore the contact 1085 thereof is engaging the contact 1087. Hence, circuit continues through the conductor 1208, Figs. 56 and 54, to a terminal 1209 and thence through conductor 1210 to one end of the winding of the solenoid 831 and thereafter through conductor 1211 to terminal 1105 and thence to ground through conductor 1106.

With the main switch shaft 802 thus set in operation upon energization of the solenoid 831, normal automatic operation of the machine may proceed primarily under control of the switch discs 1026 on the shaft 802. However, in this third preliminary cycle of operation, the relay 1098 is energized and most of the circuits closed through the intermediary of switch discs 1026 are opened by the opening of contacts on this relay, which will be apparent from the description of these control circuits set forth hereinafter.

This third preliminary cycle of operation is primarily effected to advance the first sheet in the series thereof from the sheet feeder SR, Fig. 1, into printing station in association with the main platen MP. Therefore in this third preliminary cycle of operation, the switch disc 1026d, Fig. 54, is effective to close circuit between the blades 1210' and 1211' associated therewith which is effective to energize the solenoid 1212, Fig. 55, included in the sheet feeder SR and which is effective to control a one-revolution clutch of the character, for example, shown and described in my aforesaid copending application Serial No. 239,561. Such energization of the solenoid 1212 sends the sheet feeder SR through a cycle of operation which is effective to cause a sheet to be fed therefrom into cooperating relation with the sheet feeding rollers 854, Fig. 2, which at this time will be rotating inasmuch as they are directly driven from the main drive shaft 90, as explained hereinabove.

The circuit which is thus closed to the solenoid 1212 extends from battery B4, Fig. 54, through conductor 1115, terminal 1116, conductor 1213, blade 1210', contact strip on the disc 1026d, blade 1211', conductor 1214, Figs. 54 and 55, to one end of the winding of the solenoid 1212 and thence to ground through conductor 1215 from the other end of the winding of this solenoid.

It is to be understood that among the circuits which are opened by energization of the relay 1098, Fig. 54, is the circuit which is effective, in the automatic operation of the machine, to bring about energization of the solenoid 170 which, when energized, causes the shaft 117 and the switch discs 1020 associated therewith to make a complete revolution. Hence since this circuit is open in the third preliminary cycle of operation of the machine, no printing and control devices are advanced because this is effected only when the shaft 117 is caused to make a complete revolution. Therefore, at the end of the third cycle of operation, printing and control devices which were moved into stations II and III in the second preliminary cycle remain in these stations to be available in the normal automatic operating cycle which automatically follows the third preliminary cycle.

It will be remembered that the main clutch MC is of the one-revolution type and therefore, as the main switch shaft 802 completes its rotation in this third preliminary cycle of operation, this clutch is disengaged to bring this shaft to rest. Moreover, as the shaft 802 approaches its normal at rest position, the contact strip on the switch disc 1026a moves from association with the cooperating blades 1113 and 1114 associated therewith, and this is effective, in the manner explained hereinabove, to break the stick circuit for the relay 1098, Fig. 54, which is only energized in this third preliminary cycle of operation or similar operations in the course of operation of the machine. It will be remembered that the energizing circuit to the relay 1098 is closed upon

closure of the switch 1095, Fig. 54, and that this switch is only momentarily closed to initiate the third preliminary cycle of operation. Therefore when the stick circuit for the relay 1098 is broken, this relay is deenergized and the contacts associated therewith which were opened to suspend certain normal operative functions of the machine in this third preliminary cycle are closed so that in the subsequent normal automatic operating cycles of the machine, these circuits will be effective.

First normal automatic operating cycle

Each normal automatic operating cycle of the machine automatically follows another such cycle in the normal operation of the machine and such a cycle also normally follows the aforesaid third preliminary cycle. Such a normal automatic operating cycle is automatically initiated if the contacts of the relay 1080, Fig. 56, are latched as they will be unless a detector pin as 426, Fig. 20, cooperates with a tab TB on a printing and control device at station II at the time explained above when this is effected. The cooperative functioning of the components of the machine in its normal cycle is illustrated in the timing chart afforded by Figs. 61 and 61A of the drawings, while different sequences of normal cycles and skip cycles are illustrated in the timing charts of Figs. 62, 63 and 63A so as to show the manner in which the machine is operated and controlled in the attainment of the desired automatic and continuous operation.

Thus, with reference to the aforesaid timing charts, it is to be noted that the relay 1080 is energized and latches up in one cycle of operation, as indicated in Fig. 61, whenever impressions are to be made from the printing and control device that is in station II in this cycle of operation but which is advanced to station III near the end of this cycle of operation. However, when a printing and control device so located bears a tab TB, no impressions are to be made therefrom when this printing and control device reaches station III, and when such a printing and control device bears a tab TB the switches 435, Fig. 57, are caused to so operate that the relay 1080 is not energized, as indicated in Fig. 62.

Moreover, a normal automatic operating cycle will be initiated if the relay 1190 is energized and this relay remains energized, as indicated in Fig. 61, unless the aforesaid stick circuit therefor is broken. In the present instance it will be assumed that the printing and control device which is now in station III does not bear a tab TB and furthermore it will be assumed that no improper operation of the machine has been effected, wherefore the stick circuit for the relay 1190 remains effective. It will also be understood that the shell 1136 of the start-stop switch 1135 will not have been depressed. With the machine so arranged, a normal automatic operating cycle follows the above described third preliminary cycle.

The first printing and control device in the series thereof passing through the machine is now disposed in station III in operative association with the main platen MP as is the first of the series of sheets as S that are to pass through the machine. Furthermore, the pins 442, Fig. 37A, moved into digit representing positions in the second preliminary cycle described hereinabove, are still in these digit representing positions for the reason that the Bowden cable restoring solenoid 472, Fig. 37A, was not energized in the third preliminary cycle of operation because

the shaft 107 did not rotate and therefore the switch discs as 1020 did not function and therefore the switch disc 1020a did not act to close circuit to this restoring solenoid 472.

Thus, since a check or sheet S is disposed in operative relation with the main platen MP during the first normal automatic operating cycle of the machine and since the first printing and control device is disposed in station III in association with this platen, the main platen MP is caused to operate, as explained hereinabove, in this and all normal automatic cycles of operations of the machine to make four reciprocations, in the first two of which changeable data A are printed on the check S and in the last two reciprocations of which the variable data V1 and V2 are printed thereon, and all of these operations occur in substantially the time relationship shown in the timing chart of Fig. 61.

By reason of the fact that the relay 1190 is energized at the time a normal automatic operating cycle of the machine is to be initiated and by reason of the fact that at the time such a cycle is to be initiated the switch disc 1026c is disposed in such position that the contact strip thereon is closing circuit between the blades 1202 and 1203 associated therewith, circuit is established to the solenoid 831 to thereby set the main switch shaft 802 in operation, in the manner explained above, and as indicated in Fig. 61.

It is to be remembered, however, that the shaft 104 on which the main clutch MC, controlled by the solenoid 831, is mounted makes two revolutions to one revolution of the switch shaft 802 when the machine is arranged, as in the present instance, for duplicate operation, in the manner that has been explained hereinabove. It is therefore necessary to prevent the pin on the collar or sleeve 829 of the clutch MC, Fig. 41, from engaging a cam surface on the cam plate 831', Fig. 41, controlled by the solenoid 831, at the time the shaft 104 completes the first of the two revolutions such shaft makes for each revolution of the switch shaft 802.

Therefore, a switch disc 1026e is provided on the shaft 802 and at a time in the course of rotation of the shaft 802 related to that at which the shaft 104 is about to complete its first revolution, a contact strip on this switch disc moves into circuit closing relation with the blades 1220 and 1221 associated therewith. Thereupon circuit is closed from battery B4, Fig. 54, through conductor 1115, terminal 1116, conductor 1223, blade 1220, contact strip on switch disc 1026e, blade 1221, conductor 1224 and terminal 1209 through conductor 1210 to the winding of the solenoid 831 and to ground through conductor 1106. This brings about energization of the solenoid 831, as indicated in Fig. 61, and is effective to prevent disengagement of the main clutch MC at the end of the first revolution of the shaft 104. However, just before the shaft 104 completes its second revolution the cam plate 831' is effective to bring about disengagement of the clutch MC for at this time the contact strip on the switch disc 1026e will be out of cooperating relation with the blades 1220 and 1221. However, shortly thereafter the contact strip on the switch disc 1026e moves into cooperating relation with the blades 1202 and 1203 associated therewith so that if the relay 1190 is energized another normal automatic operating cycle will be initiated because circuit is thereupon closed to the solenoid 831, as indicated at 360° in that line of the timing chart of Fig. 61 that pertains to the solenoid 831.

Inasmuch as the first printing and control device is now disposed in association with the main platen MP and since the first sheet S is also disposed in operative association with this platen with the leading edge thereof in engagement with the stop finger 850, Fig. 2, to thereby be disposed in position to receive the changeable data A on the main body Sm, it is necessary to set the main platen MP in operation in order that such impression will be made.

Therefore, a switch disc 1026f is provided on the main switch shaft 802 and this switch disc bears four contact strips disposed thereon in properly spaced apart relation to so cooperate with the blades 1226 and 1227 associated therewith that the main platen MP will, at the proper times in the course of rotation of the shaft 802 as indicated in Fig. 61, be caused to make four reciprocations that are required to produce the four impressions on the check S. Hence, shortly after the switch shaft 802 starts its revolution, the first of the contact strips on the disc 1026f is effective to close the circuit through the blades 1226 and 1227 and in such circumstance circuit is established from battery B4, Fig. 54, through conductor 1115, terminal 1116, conductor 1117, terminal 1118, conductor 1228 to contact 1131 of the relay 1098 which at this time, because this relay is deenergized, will be engaged with the contact 1130. This circuit is continued on from the contact 1130, through conductor 1229 to blade 1226, through the aforesaid contact strip on the switch disc 1026f, blade 1227, conductor 1232, closed switch 1233, terminal 1234, conductor 1235 to terminal strip 1236. From the terminal strip 1236 the circuit is continued through conductor 1237 to blade 1238 in the switch set 1240 described more fully hereinafter. At this time a contact on the blade 1238 is in engagement with a contact on the blade 1239 and therefore circuit is extended through the blade 1239 to conductor 1241 to one end of the winding of the solenoid 271, Figs. 54 and 9, that controls the clutch which is effective to set the pump 259 in operation to thereby cause the platen MP to be reciprocated, the other end of the winding of the solenoid 271 being connected to ground through the conductor 1242. The platen MP thus operates to produce the first impression of the data A on the sheet S at substantially the time indicated in Fig. 61.

Subsequent to the first printing operation of the platen MP, effected as just described, the cam shaft 300 causes the stop finger 850 to be raised, Fig. 61, and the stop finger 851 to be lowered. Thereupon the rollers 854 advance the check S into engagement with the stop finger 851 to thereby dispose the stub Sb in position to receive an impression from the printing and control device at station III. Thereupon a second contact strip on the switch disc 1026f, Fig. 54, closes the above described circuit to the solenoid 271, Fig. 54, and thereupon the main platen MP is again set in operation. In this operation of the platen MP, which takes place at substantially the time indicated in Fig. 61, the changeable data A are printed on the stub Sb. The two additional reciprocations to be imparted to the main platen MP are to be subsequently effected and by the time these two reciprocations are to be effected, under control of the third and fourth of the four contact strips on the disc 1026f, the type segments TS1 and TS2, Figs. 26 and 27, will have been set up by reason of the fact that the multiplying mechanism M will have been set in operation and

111

the setup devices operated therefrom will have been effected through the slides 555 to have disposed type characters on type segments TS1 and TS2 in position as to print the variable data V1 and V2 in accordance with the coded perforations 85 on the printing and control device that is now located at station III.

In this respect it will be remembered that the pins 442, Fig. 37A, were set in digit representing positions at the time the printing and control device now at station III was located in station II but, as explained hereinabove, the multiplying mechanism M was not set in operation, nor were the Bowden cables 357 which were effective to dispose the pins 442 in such digit representing stations restored, because the solenoid 472, Fig. 37A, for effecting this will not have been energized since the time when the pins 442 were disposed in these digit representing stations.

In order to enable the multiplying mechanism M to set up the type segments TS1 and TS2 under control of the coded perforations 85 in the printing and control device which is now at station III, the multiplying mechanism M is set in operation, Fig. 61, shortly after the main switch shaft 802 is set in operation in the course of a normal automatic operation of the machine. To this end a switch disc 1026g, Fig. 54, is included in the set of switch discs 1026 mounted on the shaft 802. This disc 1026g carries a contact strip that closes circuit between the blades 1243 and 1244, Fig. 54, when the multiplying mechanism M is to be set in operation. The circuit that is thus closed extends from battery B6, Fig. 54, through conductor 1245, blade 1243, contact strip on the disc 1026g, blade 1244, conductor 1246, contact 1126 of the relay 1098, which, since this relay is deenergized at this time, is engaged with the contact 1127 of this relay. From the contact 1127, the circuit is continued through conductor 1247, Figs. 54, 56 and 57, to contact 1058 of the relay 1052 which at this time is engaged with the contact 1056 of this relay since at this time the relay 1052 will be deenergized provided, of course, that the printing and control device now disposed at station II is properly located therein. From the contact 1056 circuit is extended through conductor 1248, Figs. 57 and 55, to a terminal strip 1249. This circuit is further extended from the terminal strip 1249 through conductor 1250 to one end of the winding of the solenoid 570, Figs. 24C and 55, of the clutch that is operative to set the main cam clutch 569 of the multiplying mechanism M in operation at substantially the time indicated in Fig. 61A. The solenoid 570 energizes at this time by reason of the fact that the circuit extended thereto, as aforesaid, is continued to ground through the conductor 1251, Fig. 55, to a terminal block 1252 and thence through conductor 1253 and the normally closed switch 1254 to ground through the conductor 1255.

In an instance where the printing and control devices are to be passed through the machine, for example, to be used in the preparation of proxy notices in which event there will be no need to operate the multiplying mechanism M, since the printing and control devices will be merely used as printing devices in such an instance, the switch 1254, Fig. 55, which is located at a convenient place in the machine, is opened which, it will be appreciated, will prevent the solenoid 570 from being energized, wherefore the multiplying mechanism M will be prevented from operating.

However, when the multiplying mechanism M

112

is set in operation in the manner described, it is effective through the Bowden cables 515, Fig. 26, and the devices associated therewith to set the pinions 532 in digit representing positions and, as explained hereinabove, in the course of the operation of the multiplying mechanism M, the cam 546, Fig. 26, on the cam shaft 499 of the multiplying mechanism M actuates the cam plates 525 and 526, Fig. 26A, in a manner hereinabove explained, to move the pinions 532 into engagement with the racks 554 on the rack slides 555. Thereafter the printing unit 600 is set in operation to bring about setup of the interconnected slides 555 and 555r and thereby set the type segments TS1 and TS2 in position to print the variable data V1 and V2 on the check as S and web W.

Therefore, subsequent to the time the multiplying mechanism M is set in operation and at a time 20 in the course of a cycle of operation of this mechanism subsequent to the time, Fig. 61A, at which the summation members 375 therein attain their digit representing positions, the clutch of the solenoid 577, Fig. 25, which controls the clutch 25 that is effective to set the cam shaft 560 of the printing unit 600 in operation, is energized to enable this cam shaft to make a complete revolution.

Inasmuch as the printing unit 600 in a normal 30 cycle of operation is only to be operated in those circumstances where the multiplying mechanism M has operated, the circuit for energizing the solenoid 570 is controlled from one of the switch discs 1166, Figs. 55 and 34, operated from the shaft 499 of the multiplying mechanism M. To this end a switch disc 1166b is included in the set of discs 1166 and a contact strip on this switch disc is effective to close circuit between blades 1256 and 1257 associated therewith to the solenoid 577.

In such an instance circuit is extended from battery B7, Fig. 55, through conductor 1258, blade 1257, contact strip on the switch disc 1166b, blade 1256, conductor 1259 to terminal strip 1260. Circuit is continued from the terminal strip 1260 through the conductor 1261, the winding of the solenoid 577, Figs. 25 and 55, conductor 1262, terminal strip 1252 and thence through conductor 1253 closed switch 1254 and to ground through conductor 1255.

In instances where the machine is to be operated in such a way as to enable a list to be printed upon operation of only the proofer platen PP, in which instances it may not be desirable to operate 55 the multiplying mechanism M, the switch 1254, Fig. 55, which is located at a convenient position in the machine, is opened and so to do prevents energization of either the solenoid 570, which controls the clutch for the multiplying mechanism M, or the solenoid 577, which controls operation of the printing unit 600.

Upon such energization of the solenoid 577, in the manner above described, the cam shaft 560 of the printing unit 600 makes a complete revolution in the course of which, in the manner hereinabove explained, the type segments TS1 and TS2 are set in such positions that the variable data V1 and V2 may be printed on the check S and the web W.

70 The variable data V1 that the type segments TS1 and TS2 are thus set to print is the product of the variable factor represented on the printing and control device, which was effective to set the pins 442 in position to control the operation of the multiplying mechanism M, and the reoc-

curring factor employed in forming the templets TP. It will be recalled that the printing and control device, which effected this setup of the pins 442, was disposed in station II when such setup was effected and that this printing device has been advanced to station III and is disposed in this station in the cycle of operation in which the multiplying mechanism M operates in response to the aforesaid setup of the pins 442. Thus the two impressions of changeable data A that are made on the sheet that is now disposed in association with the main platen MP are made from the printing and control device which determined the setup of the type segments TS1 and TS2 in this cycle of operation in which the data determined from such printing and control device are to be printed from the setup type segments TS1 and TS2. It will be understood that in the last two of the aforesaid four reciprocations of the platen MP, the type segments TS1 are set up in pursuance of the data derived from the aforesaid printing and control device. This therefore insures that the changeable data A and the variable data V1 which are printed on the particular check associated with the main platen MP are related one to the other. Moreover, it will be understood that the variable data V2 are printed from type segments TS1 and TS2, that are set up simultaneously with those type segments from which the variable data V1 are printed but those type segments from which the variable data V2 are printed are set up under control of devices included on the plate 710, Fig. 38, as explained hereinabove.

It will be recollect that the slides 555f and the type segments TS2 that are actuated thereby are set up and restored to their zero positions in a cycle of operation of the printing unit 600 that is effected under control of the switch disc 1166b, Fig. 55. It is, therefore, necessary to operate the platen PP so as to make an impression from the setup type segments TS2 and this is done intermediate the time the type characters TCf are set to print the variable data V1 and V2 and the time that they are restored to their normal zero positions, as indicated in Fig. 61. Therefore, in a cycle of operation of the printing unit 600 in which the type segments TS1 and TS2 are set up from and under control of a circuit closed through the aforesaid switch disc 1166b, the pager and proofer platen PP is set in operation under control of a switch disc included in the group of switch discs 1263, Figs. 55 and 36, that are operated from the cam shaft 560 of the printing unit 600.

The circuit which is thus closed to set the platen PP in operation is extended from battery B8, Fig. 55, through conductor 1264, blade 1265, a contact strip on the switch disc 1263a, blade 1266 associated with this switch disc, conductor 1267, Figs. 55 and 54, to the terminal strip 1268, Fig. 54. From the terminal strip 1268, the circuit is extended through a conductor 1269 to one end of the winding of the solenoid 272, Figs. 54 and 9, and thence to ground through the conductor 1270. The solenoid 272 controls operation of the clutch which in turn controls operation of the pump 260 that is effective to operate the pager and proofer platen PP. Therefore energization of the solenoid 272, as indicated in Fig. 61A sets this platen in operation, whereupon the variable data V1 and V2 are printed on the web W at what is to be the top of the first proof sheet as PS1.

In the present operation of the platen PP, a

printing and control device will not have been advanced to station V and it is therefore desirable to render the printing face 301, Fig. 24, of the platen PP ineffective. To this end the solenoid 321, Figs. 24 and 54, is energized in this first normal cycle of operation of the machine as it is in every other cycle of operation of the machine in an instance where a printing and control device is not disposed at station V that is to have an impression made therefrom. Furthermore, as will be explained presently, when a printing and control device is selected under operation of the selector including the switch pile 435, impressions will not be made from such a printing and control device in either station III or station V and whether or not an impression is to be made from a printing and control device in station V is determined prior to the time the printing and control device reaches such station.

It will be recollect that the selector including the switch pile 435 is located at station II and it will be understood that when it is determined that an impression is not to be made from such a printing and control device, it will thereafter, in the same cycle of operation in which this is determined, advance to station III. Furthermore in still another succeeding cycle of operation, this printing and control device will be advanced to station V. Hence, two cycles of operation of the machine intervene before a printing and control device from which an impression is not to be made reaches station V.

When an impression is not to be made from a printing and control device because it is selected to be skipped, the selector functions, as will be explained, to set up devices which will prevent operation of the main platen MP in the succeeding cycle of operation of the machine. However, the printing and control device is moved from station II where it is sensed for selection into station III in the cycle of operation in which it is sensed at station II and at the end of this cycle of operation in which this sensing is effected the printing and control device is disposed at station III. However, when the selector has functioned to render the operating devices for the platen MP effective in a particular cycle of operation, the carrier bars 121 and 122 make two reciprocations in this cycle, moving the printing and control device from station III to station IV in the first reciprocation thereof and moving this device from station IV to station V in the second reciprocation thereof. Thus two reciprocations of the carrier bars intervene in moving a printing and control device from station III to station V and therefore when no impression is to be made from a printing and control device when it attains station V, it is necessary to delay the operation which renders the printing face 302 of the platen PP ineffective to print from a printing and control device for two reciprocations of the carrier bars 121 and 122 or throughout one cycle of operation of the machine.

However, when a printing and control device is selected to be printed, the platen MP, when the printing and control device is disposed in station III, makes four reciprocations in the cycle of operation in which the printing and control device is disposed in this station. In each such reciprocation of the main platen MP it is effective to push the Bowden cable 1280, Fig. 23C, which in turn, in the manner explained hereinabove, pushes pins 1291 so as to thereby prevent these pins from cooperating with the blade 1293 of the switch 1292 when such a pin, if unpushed, would

cooperate with and close this switch. Such a pin would so cooperate with the switch 1292 after the carrier bars 121 and 122 had made two reciprocations subsequent to the time at which the Bowden cable 1280 should have been operated to push the pin. Thus in a normal cycle of operation of the machine where the main platen MP is operated, the switch 1292 is not closed when the pins so pushed move into association therewith and this is effective to enable the printing face 301 of the platen PP to remain in its effective position. Furthermore, after two such reciprocations of the carrier bars 121 and 122, the printing and control device which was at station III when the platen MP operated to push the Bowden cable 1280 is now at station V and since impressions were made from this printing and control device when it was in station III, an impression is to be made therefrom while it is at station V. It is for this reason that the printing face 301 of the platen PP is permitted to remain in effective position in those instances where the switch 1292 is not closed because the pins 1291 which move into cooperation therewith have been pushed.

The particular manner in which the pins 1291 are pushed or not pushed and the manner in which these pins are advanced from the station whereat they are pushed or not pushed into the station where they cooperate with the switch 1292 has been explained hereinabove.

Now in so far as the present first normal automatic operating cycle of the machine is concerned, which ensues after the aforesaid three preliminary cycles, carrier bars 121 and 122 have made two reciprocations, one in the first preliminary cycle and the second in the second preliminary cycle, for as stated hereinabove, in the third preliminary cycle, operation of the carrier bars 121 and 122 is suspended. In this respect the first two preliminary cycles differ from those cycles of operation in the normal automatic operation of the machine for in the normal automatic operation of the machine the carrier bars 121 and 122 make two reciprocations in the course of each cycle of operation, there being an exception to this in an instance where a printing and control device is to be skipped, as will be explained. Moreover, in none of the aforesaid three preliminary operations of the machine was the main platen MP operated. Therefore, since the rocker 150 operated once in the first preliminary cycle and again in the second preliminary cycle, two unpushed pins 1291 will have been advanced by the pawl 1286, Fig. 10, on the rocker 150. Hence, in this first normal cycle of operation of the machine the first of these pins will be closing the switch 1292 and it is closure of this switch that effects retraction of the printing face 301 of the platen PP from its normal operative position, this being effected by closure of a circuit to the solenoid 321, Figs. 23, 24 and 54.

In this instance circuit is extended from the battery B25, Fig. 54, through a conductor 1296 to the blade 1293 of the switch 1292 and since a pin 1291 will at this time be closing the switch 1292 the contact on this blade 1293 is engaged with a contact on the blade 1294 and therefore circuit is continued on through to conductor 1298, Figs. 54 and 55, to the terminal strip 1299. A conductor 1300, Figs. 54 and 55, leads from the terminal strip 1299 to one end of the winding of the solenoid 321, the other end of the winding of this solenoid being connected to ground through the conductor 1301. In the manner explained

hereinabove, energization of the solenoid 321 causes the cam shafts 314, Fig. 24, to be rotated in such position that the springs 313 may render the printing face 301 ineffective.

Furthermore, when the machine is first set in operation, the numbering devices 880 and 881, Fig. 25, have the type wheels thereon disposed in such position that if the numbering devices were not caused to advance they would print a number one less than that desired to be printed in the first operating cycle of the machine. For example, if the first number to be printed was 1 these devices would be zeroized. Therefore, shortly after the multiplying mechanism M is rendered effective, in the manner explained hereinabove, the cam 892, Fig. 25, causes the printing wheels of the numbering devices to be advanced into position to print the number desired on the first check or stub S and in the third and fourth of the aforesaid four reciprocations of the main platen MP, the numbering device 880 is effective to print the number N first on the stub Sb and thereafter on the main body SM of the first check S.

Moreover, the numbering device 881 is to be effective to print a corresponding number on the web W in association with the first impressions of the variable data V1 and V2 made thereon in the aforesaid operation of the proofer platen PP.

In order to enable this to be effected, the solenoid 342, Figs. 23 and 54, must be energized. To this end a switch blade 1026h, Fig. 54, is provided on the main switch shaft 802 and includes a contact strip which is effective to close circuit between the blades 1302 and 1303. Circuit between these blades is established at a time in the course of rotation of the shaft 802 related to the time at which circuit is closed to the solenoid 272, Fig. 54, to cause the pager and proofer platen PP to make an operation.

In this instance circuit is extended from battery B4, Fig. 54, through conductor 1115, terminal 1116, conductor 1223, blade 1302, the contact strip on the disc 1026h, blade 1303, conductor 1304 to one end of the winding of the solenoid 342 and thence to ground through a conductor 1305. Such energization of the solenoid 342 disposes the printing face 304 of the platen PP in effective position and therefore an impression is made from the numbering device 881.

It will, therefore, be seen that when the platen PP is rendered operative in this first normal automatic operating cycle only the printing faces 302 and 304 thereon are effective for, as explained hereinabove, the printing face 301 is retracted to an ineffective position and consequently in this first operation of the platen PP the variable data V1 and V2 and the number N are printed on the web W.

As stated hereinabove, when the machine is operating automatically and the carrier bars 121 and 122 are operated so as to effect two reciprocations thereof as in the present instance, resort is had to this arrangement so as to enable a printing and control device that is disposed at station III in one cycle of operation to be disposed in station V in the succeeding cycle of operation. It is necessary to do this for in one cycle of operation when the variable data V1 and V2 and the number N are printed on the web W, the portion of the web that receives these impressions is one step away in the step-by-step advancing of the web from the position whereat an impression will be made thereon by the printing face 301 of the platen PP from a printing and control device

disposed at station V. Thus in so far as the web is concerned, the variable data derived from a particular printing and control device is printed in one cycle of operation and the changeable data A derived from this particular printing and control device is printed on the web W in the succeeding cycle of operation.

Therefore, after the variable data V1 and V2 have been printed on the web W, in the course of the aforesaid operation of the platen PP, the means for advancing the web W included in the pager and proofer mechanism PM are rendered operative to bring about an advancing movement of the web, Fig. 61A. To this end circuit is closed to a solenoid 923, Fig. 55, which is effective to send the pager and proofer mechanism through a single operation, as described hereinabove, to advance the web, this solenoid, as explained, causing a one-revolution clutch to be engaged. Inasmuch as the variable data as V1 and V2 will only be printed on the web W in an instance where the printing unit 600 is caused to make a cycle of operation, advancing movement of the web W is controlled from this printing unit. To this end a switch disc 1263b is included in the set of switch discs that are operated from the cam shaft 560 of this unit. The circuit that is closed in such an instance is extended from battery B8, Fig. 55, through a conductor 1264 to the blade 1305 associated with the switch disc 1263b and through the contact strip on this switch disc to the blade 1307 and thence through the conductor 1308 to one end of the winding of the solenoid 923, this circuit being completed to ground through the conductor 1309.

Inasmuch as the shaft 117 is to make two revolutions in each normal automatic operating cycle of the machine, circuit is closed to the solenoid 170, Figs. 55 and 10, in such cycles of operation from a source different from that in which circuit is closed to this solenoid in the aforesaid first and second preliminary cycles, during each of which cycles this solenoid is energized but once. Therefore, a switch disc 1026i, Fig. 54, is provided in the set of switches 1026 on the main switch shaft 802 and blades 1310 and 1311 are associated with this switch in position to be engaged by the two spaced apart contact strips provided on this switch disc which move into engagement therewith at those times in the course of a normal automatic cycle when the printing and control devices are to be advanced.

Circuit is extended to the solenoid 170 in such an instance from battery B9, Fig. 54, through a conductor 1313, contact 1129 of the relay 1098, which at this time will be deenergized, and through the contact 1128 of this relay which at this time will be engaged with the aforesaid contact 1129. A conductor 1314 extends from the contact 1128 to switch blade 1310 so that circuit is extended through, in this instance, the first of the aforesaid contact strips on the switch disc 1026i to the switch blade 1311 and thence through conductor 1315, Figs. 54 and 55, to the terminal block 1014. In such circumstance circuit is closed through the winding of the solenoid 170 from the terminal block 1014 through conductor 1015 and conductor 1016 past closed switch 1017 through conductor 1018 to ground.

In this respect it is to be noted that the manually-operated switch 1017, Fig. 55, is located at a convenient position in the machine to enable the means for advancing the printing and control devices through the machine to be rendered inoperative, as in the instance where it is de-

sired to make a large number of impressions, for example, from a printing and control device advanced to station III. At all other times in the operation of the machine, the switch 1017 remains closed.

It will be understood that when the solenoid 170 is energized in the aforesaid manner, Fig. 61A, the carrier bars 121 and 122 make the first of the two reciprocations thereof that are required in a normal operating cycle of the machine. The second of the reciprocations of the carrier bars 121 and 122, Fig. 61A, is effected when the second of the contact strips on the switch discs 1026 moves into association with the blades 1310 and 1311.

In this respect it is to be noted that while the carrier bars make two reciprocations in each cycle of operation of the machine, all of the printing and control devices associated therewith are not to be advanced in each of such reciprocations. The primary reason for causing the carrier bars 121 and 122 to make two reciprocations in the course of a normal cycle of operation of the machine is to insure the advancing of a printing and control device from station III to station V in a single cycle of operation. Therefore, in the first of the reciprocations effected, as aforesaid, by the carrier bars 121 and 122, only the printing and control device that is disposed in station III is to be advanced and prior to the time this printing and control device is so advanced, the platen MP will have made the first two of the four reciprocations thereof, as described above, so that changeable data A will have been printed on both the main body Sm and the stub Sb of the check S.

In order to prevent the printing and control devices in station I and II from being advanced from these stations in the first of the aforesaid reciprocations of the carrier bars 121 and 122, the solenoid 208, Figs. 19 and 56, is energized, as indicated in Fig. 61, to render the pawls 180 and 181, and 211 and 212, ineffective. This, it will be remembered, is effected by causing a finger 191, Fig. 21, to engage the ends 192 of the spring 193 carried by the rocker 194. It has also been explained, that the rocker 194 is pivoted into the lower broken-line position thereof shown in Fig. 22 when the ends 192 of the springs 193 are to be ineffective to shift the rocker 196 on which the finger 191 is included, and this, as has been explained, is brought about by energization of the solenoid 208.

Therefore, in the course of the first of the aforesaid two reciprocations of the carrier bars 121 and 122 circuit is closed to the solenoid 208 and this is effected under control of a switch plate 1026j, Fig. 54, included in the set of switches 1026 on the main switch shaft 802. This circuit is extended from the battery B4 through conductor 1115, terminal 1116, conductor 1223 to blade 1316, thence through the contact strip on the switch disc 1026j to blade 1317, and thence through conductor 1318, Figs. 54 and 56, to one end of the winding of the solenoid 208 and thence through conductor 1319 to terminal 1320 and thereafter through conductor 1033 to ground at 1031. However, the circuit through the contact strip on the switch disc 1026j is only sufficiently prolonged to maintain the solenoid 208 energized during the first of the aforesaid two reciprocations of the carrier bars 121 and 122. Therefore in the second of such reciprocations of the carrier bars, they are effective to advance a printing and control device from station I and

station II, from station II to station III and from station IV to station V, this latter being the printing device that was advanced from station III to station IV in the first reciprocation of the carrier bars 121 and 122 in a cycle of operation.

It will be appreciated that the cable restoring solenoid 472, Fig. 37A, must be energized at least once in every cycle of operation of the machine and it has been explained hereinabove that this is effected in the early part of a cycle of operation and at a time after the positioning templets PT have cooperated with pushed pins 442. Inasmuch as such cable restoring must even be effected in instances such as the first and second preliminary cycles discussed hereinabove, the disc 1020a is included in the set thereof connected to the shaft 117 for it will be remembered that it is the shaft 117 that is effective to operate the detecting head 352.

However, in the normal automatic operating cycles of the machine, the shaft 117 makes two revolutions but in such an instance it is necessary that the cable restoring solenoid 472 be energized only during the first of such revolutions of the shaft 117. It is for this reason that the circuit to the solenoid 472 is extended to the switch disc 1026k, Fig. 54, in the set thereof on the main switch shaft 802. In such cycles of operation as are effected when the switch shaft 802 is at rest, the contact strip on the switch disc 1026k is effective, as explained hereinabove, to enable the circuit to the solenoid 472 to be established for at that time this contact strip is in engagement with the blades 1025 and 1027 that cooperate therewith.

However, in a normal automatic operating cycle of the machine, the contact strip on the disc 1026k moves out of engagement with the blades 1025 and 1027 associated therewith prior to the time the solenoid 170 is energized to cause the shaft 117 to make the second of the revolutions thereof that are effected in a normal automatic operating cycle. Consequently, in such second revolution of the shaft 117, the disc 1020a is ineffective to close circuit to the solenoid 472, Fig. 61, for this circuit is opened at this time by the disengagement of the contact strip on the disc 1026k from the blades 1025 and 1027.

It is of course important to insure that a sheet as S is fed into the machine and is in operative association with the main platen MP. Therefore, sheet safety circuits are provided which are effective to ascertain whether or not the sheets as S are in proper position in the sheet guideway SG.

As has been explained hereinabove, after the main platen MP has made the fourth of the aforesaid reciprocations thereof to print the variable data V1 and V2 on the main body Sm of a check S, the sheet that has received these impressions passes along the sheet guideway SG toward the printing unit PC, and this occurs near the end of a cycle of operation of the machine. Furthermore, near the end of such a cycle of operation of the machine, the sheet S that is to receive impressions in the succeeding cycle is fed into the machine and in the event a sheet is not so fed, it is necessary to insure that the ensuing automatic cycle of operation of the machine be prevented.

To this end a frame 1400, Figs. 2 and 2A, is mounted on the table top TT immediately in front of the point whereat the sheets S are discharged from the sheet feeder SR, and a lever 1401 is pivotally mounted on this frame, as indicated at

1402. A roller 1404 is provided at the free end of this lever and the opposite end thereof bears on a cam 1405 on the cam shaft 300. At a predetermined time in the course of rotation of the cam shaft 300 which, as explained hereinabove, makes one complete revolution in each cycle of operation of the machine, a rise on this cam moves into engagement with the end 1406 of the lever and thereupon the roller 1404 is forced toward the bottom of the sheet guideway SG afforded on the table top TT. An opening 1407 is provided in the bottom of the sheet guideway SG in alignment with the roller 1404 and a block 1408 of fibrous material is supported by a leaf 1409 of the switch, generally indicated by 1410, to be held in position in the guideway 1411 therefor supported from the table top TT. The guideway 1411 has a slot 1412 therein and a pin 1413 on the block 1408 is disposed in this slot and engagement of this pin with the upper end of this slot limits the upper position into which the block 1408 may move.

The roller 1404 has a pair of flanges 1414 and 1415 thereon which, in the event a sheet S is not disposed beneath the roller 1404 at the time the cam 1405 acts to lower this roller, move into a pair of slots 1416 and 1417 in the upper edge of the block 1408. When the flanges 1414 and 1415 move into the slots 1416 and 1417, the lowering movement imparted to the roller 1404 is ineffective in so far as the contacts included in the switch 1410 are concerned.

However, if a sheet S is discharged from the sheet feeder SR at the time in the course of operation of the machine when this should be effected, then when the cam 1405 forces the roller 1404 downwardly it moves into engagement with the sheet and in this instance it is effective through the sheet to force the block 1408 downwardly in the guideway 1411 therefor. Such movement of the block 1408 downwardly in the guideway 1411 forces a contact on the blade 1409 into engagement with a contact on the blade 1418 and in certain embodiments of my machine this is utilized for effecting the operation of a unit as 1775, Fig. 55, which may be incorporated therein for the purpose of printing a signature B on a sheet as S. In the present embodiment of my invention, however, the contacts 1409 and 1418 are ineffective for I utilize means including the printing unit PC for printing a signature B on the check as S in place of the unit 1775.

However, it will be noted that contacts on the blades 1419 and 1420 of the switch 1410 are normally engaged, and a pin of fibrous material 1421 is extended from the blade 1409 to the blade 1420 and if the block 1408 is forced downwardly when a sheet S is disposed between this block and the roller 1404, the contact on the blade 1420 is moved from engagement with a cooperating contact on the blade 1419. This is effective to so condition a circuit that an impulse cannot be sent therethrough to energize the relay 1195, Fig. 56, through the contacts 1194 and 1196 of which the stick circuit for the relay 1190 is established.

An impulse is not sent through the circuit that is opened by disengagement of a contact on the blade 1420 from a contact on the blade 1419 until near the end of a cycle of operation of the machine so that circuit will not be broken to the relay 1195, and therefore to the relay 1190, until shortly before an operation of the machine should be interrupted because of the fact that a sheet S should not be advanced into the machine until

this time. The circuit through which an impulse is so sent extends from battery B10, Fig. 54, through a conductor 1425 to a blade 1426 associated with a switch disc 1026m on the timing switch shaft 802 and it is a contact strip on this disc that moves into engagement with the blade 1426 associated therewith at the time an impulse is to be sent through the circuit. The circuit is extended from the contact strip on the switch disc 1026m through the other blade 1427 associated therewith through a conductor 1428, Figs. 54, 56 and 57, to the blade 1420 and therefore if a sheet S is disposed between the block 1408 and the roller 1404 to disengage a contact on the blade 1420 from a cooperating contact on the blade 1419, circuit is interrupted at this point and is not continued on to the relay 1195.

If, however, no sheet is present and the block 1408 remains in its aforesaid upper position, then the contact on the blade 1420 is engaging the contact on the blade 1419, and in such circumstance, when an impulse passes over the circuit to the blade 1420, as aforesaid, this circuit is extended from the blade 1419 through conductor 1429, Figs. 57 and 56, to a terminal strip 1430. A conductor 1431 extends from the terminal strip 1430 to one end of the winding of the relay 1195, and a conductor 1432 leads from the other end of this winding to a terminal 1433. From the terminal 1433 circuit is extended through a conductor 1434 to ground. It will therefore be seen that if the contacts on the blades 1419 and 1420 are in engagement because no sheet has been fed into association with the roller 1404, then the relay 1195, Fig. 56, is energized whereupon the contacts 1194 and 1196 thereof are disengaged and thereupon the stick circuit for the relay 1190 is broken so that, at the end of the ensuing cycle, operation of the machine is interrupted.

Furthermore, if a sheet S does not advance into proper operative relation with the main platen MP, a detector finger 1435, Fig. 54, that is operated under control of a cam (not shown) included on the cam shaft 300, is rendered effective, prior to the time the main platen MP is caused to effect the first of the aforesaid four reciprocations thereof in a cycle of operation of the machine. If a sheet is not in proper operative relation with the platen MP, the detecting finger 1435 passes through an opening in the bottom of the sheet guideway SG and engages the blades 1436 and 1437 of the switch 1438 that is carried by the table top TT in position to cooperate with this finger. Closure of this switch is effective to close a circuit which brings about immediate interruption of operation of the machine.

In this instance, circuit is extended from battery B11, Fig. 55, through a conductor 1438' to a normally closed switch 1439. In this respect the switch 1439 is located at a convenient position in the machine so that in those instances where only the pager and proofer mechanism PM and the platen PP are to be operated to prepare a list, the detecting finger 1435 will be ineffective to interrupt operation of the machine for in such circumstances no sheets are fed through the sheet guideway SG and the switch 1438 is therefore to be ineffective. From the normally closed switch 1439 circuit is extended through conductor 1440, Figs. 55 and 54, to the contact 1133 of the relay 1098, which contact is engaged with the contact 1132 since relay 1098 is deenergized at this time. From the contact 1132, circuit is extended through the conductor 1441 to the blade 1436 of the switch 1438. If the switch 1438 is closed under the in-

fluence of the detector pin 1435, as aforesaid, circuit is extended from the blade 1437 through a conductor 1442 to one end of a winding of a solenoid 1443, Figs. 54, 41 and 42, the other end of this winding being connected to ground through conductor 1444, terminal 1103, conductor 1104, terminal 1105 and conductor 1106.

The solenoid 1443 that is thus energized is effective to disengage the main clutch MC and is also effective to break certain operative circuits that are established in the machine. By referring to Fig. 41, it will be seen that a lever 1445 is pivotally mounted on the frame F, as indicated at 1446, and that a spring 1447 is normally effective thereon to urge the end of this lever connected to the armature 1448 of the solenoid 1443 upwardly. A rod 1449 rests on the opposite end of the lever 1445 and is extended through suitable supports therefor in the frame F and has a collar 1450 at the upper end thereof which is adapted for cooperation with a flange 1451 provided on the sleeve 829 of the main clutch MC.

Therefore, when the solenoid 1443 is energized and the armature 1448 thereof is attracted, the rod 1449 is forced upwardly and thereupon the collar 1450 thereon engages the flange 1451 so as to thereby move the sleeve 829 on the shaft 104 to disengage the clutch tooth thereon from the cooperating clutch teeth on the collar 830 and thereupon the main clutch MC is released to thereupon render the main controls for the machine, namely, the switch shaft 802 and the cam shaft 300, inoperative.

By referring to Fig. 41, it will be seen that the switches 1240 (see also Fig. 54) are carried by a bracket 1452 on the main frame F in position to cooperate with a collar of fibrous material 1453 on the rod 1449. The switches 1240 include the blades 1238 and 1239 which, as explained hereinabove, are normally engaged to establish circuit to the solenoid 271 that is effective to set the pump 259 in operation to operate the main platen MP. Therefore, when the rod 1449 moves upwardly, as aforesaid, the normally engaged contacts on the blades 1238 and 1239 are disengaged and thereupon circuit to the pump controlling solenoid 271 is broken.

It will be noted that the switch 1240 also includes a pair of blades 1454 and 1456 which have contacts thereon that are normally disengaged but when the collar 1453 engages the blade 1454, these contacts are engaged to thereby establish circuit to the relay 1195 to effect energization of this relay and thereby break the stick circuit for the relay 1190. In this instance, circuit is extended from battery B12, Fig. 54, through a conductor 1457 to switch blade 1456, and thence through switch blade 1454, conductor 1458, Figs. 54 and 56, to the terminal block 1430 from whence circuit is established, in the manner described hereinabove, to energize the relay 1195.

Furthermore, the blades 1459 and 1460 in the switch 1240 have contacts thereon which are normally disengaged one from the other but upon closing of the switch 1240, as aforesaid, these contacts are effective to establish circuit to a signal lamp 1461, Fig. 56. Circuit is extended in this instance from battery B12 through conductor 1457 to blade 1459 and thence through blade 1460, conductor 1462, Figs. 54 and 56, to one terminal of the lamp 1461, the opposite terminal of this lamp being connected to ground at 1110 and thereupon this lamp is rendered operative.

It will be noted that a manually-operated switch 1463, Fig. 54, is included in the conductor

1442 leading to the solenoid 1443 and in this respect it is to be noted that when the solenoid 1443 is energized, operation of the cam shaft 300 is interrupted and therefore the detector pin 1435, Fig. 54, maintains the switch 1436 closed to maintain the solenoid 1443 energized. However, operation of the lamp 1461 is indicative that operation of the machine has been interrupted by reason of the energization of the solenoid 1443 and when this occurs, the manually-operated switch 1463 may be opened to deenergize the solenoid 1443 and permit the rod 1449 and the parts associated therewith to be restored to their normal at rest positions. However, before the machine is again set in operation, the reason for energization of the solenoid 1443 is determined, and this erroneous condition is corrected. Thereafter the various operative mechanisms in the machine are manually restored to their normal at rest positions so as to thereby insure that proper timed relation will be maintained among the various operative mechanisms. Prior to such manual restoration of the various operative mechanisms in the machine, however, the main switch 1000, Fig. 57, is opened so as to enable such manual restoration of the various operative parts to be effected.

Normal automatic operating cycle

Normal operating cycles of the machine subsequent to the above described first normal automatic operating cycle are identical with such first cycle except in that such instances a printing and control device will be disposed at station V at the initiation of such a cycle of operation. Therefore the switch 1292 is not closed and therefore the printing face 301 of the platen PP is effective to make an impression from the printing and control device disposed at station V.

Operation to pass a printing and control device through the machine without having impressions made therefrom

As has been explained hereinabove, in the early part of a normal cycle of operation of the machine, the relay 1091 is energized, Fig. 61, to unlatch the contacts 1084 and 1086 and 1085 and 1087 of the relay 1080 whether or not these contacts have been latched so that near the end of a cycle of operation of the machine if the printing and control device still at station II is to have impressions made therefrom, the relay 1080 will be energized in a manner described hereinabove to be effective in the succeeding cycle of operation, by which time the printing and control device will be at station III, to cause impressions to be made from this printing and control device.

However, if the printing and control device disposed at station II has a tab as TB thereon in position to cooperate with the detector pin 426, Fig. 20, then prior to the time the printing and control device at station II is advanced to station III near the end of a cycle of operation, the detector head 352, Fig. 62, is lowered and upon engagement of the pin 426 with the tab TB the switches in the switch pile 435 are so operated that the hereinabove described circuit through which the relay 1080 is energized are opened so that the relay 1080 is not energized, as will be evident in that portion of Fig. 62 which illustrates a normal cycle during which a printing and control device bearing a tab TB is sensed, wherefore the aforesaid contacts thereof are not latched. Consequently, in the succeeding cycle of operation when the printing and control device bear-

ing the aforesaid tab TB is disposed in station III, the platen MP and other operative devices in the machine are not caused to function so that the setup of the pins as 442, Fig. 37A, effected from this printing and control device is not utilized and no changeable data A are printed, either in this cycle of operation or in the succeeding cycle of operation.

Thus, at the initiation of the cycle of operation in which a printing and control device bearing a tab TB is disposed at station III, the contacts 1084 and 1086, Fig. 56, of the relay 1080 are engaged because this relay did not energize to disengage these contacts. Thereupon circuit is closed to the switches 1500, Figs. 42, 54, and 62 which are driven directly from the shaft 99 that is constantly operated so long as the main drive shaft 90 is in operation. These switches are ineffective in normal cycles of operation of the machine, as indicated in Fig. 62, for the reason that circuit is not extended thereto through the contacts 1085 and 1087, Fig. 56, for in normal cycles of operation of the machine these contacts are separated by reason of the energization of the relay 1080.

The circuit that is established to the switches 1500 is extended from battery B4, Fig. 54, through conductor 1115, terminal 1116, conductor 1117 to the blade 1202 and at this time the shaft 802 is at rest and therefore the contact strip on the switch disc 1026c is closing circuit between the blades 1202 and 1203. Hence circuit is extended from the blade 1203 through the conductor 1204, Figs. 54 and 56, to the terminal 1205, and thence through conductor 1501 to contact 1502 of the relay 1080 which at this time is energized, wherefore the contact 1502 is engaged with contact 1503. This circuit is extended from the contact 1503 through the conductor 1504, Fig. 56, to the contact 1084 of the relay 1080 which, as stated, is engaged with the contact 1086. Therefore circuit is extended from the contact 1086 through the conductor 1505, Figs. 56, 57, 55 and 54, to the terminal 1506, Fig. 54.

Circuit thus extended to terminal 1506 is first effective through one of the switches 1500 to effect an operation of the platen PP in those instances where a printing and control device now at station V has had impressions made therefrom when this printing and control device was disposed at station III. To this end circuit is extended from terminal 1506 through a conductor 1507, Fig. 54, to a blade 1508 which, like the blade 1509, is associated with a switch disc 1500a in the switch 1500. In the course of rotation of the switch disc 1500a with the shaft 99, a contact strip on the disc 1500a closes circuit between the blades 1508 and 1509 and thereupon circuit is extended through the conductor 1510 from the blade 1509 to the terminal strip 1268. It will be recalled that this terminal strip is connected through a conductor 1269 to one end of the winding of the solenoid 272, the other end of which winding is connected to ground through the conductor 1270. Thereupon the solenoid 272 is energized to set the pump 260 in operation which thereupon effects an operation of the platen PP at substantially the time indicated in Fig. 62.

It is to be noted that in this cycle of operation, circuit is not closed to the solenoid 342, Figs. 24 and 54, wherefore the printing face 304 of the platen PP is retained in its retracted position, Fig. 62, and consequently a number is not printed on the web W in this operation of the platen PP.

75 It will be understood that variable data VI and

125

V2 are not printed on the web W at this time for the reason that the type segments TS1 and TS2 are not set up since neither the printing unit 600 nor the multiplying mechanism M is operated in this cycle of operation for the reason that circuit to the solenoid 831 of the main clutch MC is not closed, by reason of the fact that contacts 1085 and 1087 of the relay 1080 are disengaged since this relay is not energized and therefore the main switch shaft 802 does not operate in this cycle of operation to initiate operation of the multiplying mechanism M and therefore the printing unit 600.

It is, however, necessary in this cycle of operation to advance the printing and control devices and in a cycle of operation such as this a printing and control device is advanced from station I to station II and another printing and control device is advanced from station II to station III and the aforesaid printing and control device bearing the tab TB is advanced to station IV for in this cycle of operation the carrier bars 121 and 122 make but a single reciprocation. In this respect, it is not important in a cycle of operation such as the present one, that the printing and control device bearing the tab TB attain station V for the reason that no impression is to be made therefrom. Such a printing device, however, is advanced into station V in the succeeding reciprocation of the carrier bars 121 and 122 and in the next succeeding reciprocation of the carrier bars this printing and control device is moved into the discharge chute 231 and no impression is made therefrom while it is in station V because, even if the platen PP operates at this time, the switch 1292 will be effective to cause the printing face 301 of the platen PP to be disposed in its ineffective position.

However, in order to enable the printing and control devices to be advanced in this cycle of operation, the shaft 117 is set in operation and to this end the solenoid 170 is energized. In this cycle of operation circuit is established to the solenoid 170 from the terminal 1506, Fig. 54, through a conductor 1507a to the blade 1511a that is associated with the switch disc 1500b that also has a blade 1511 associated therewith. In the course of rotation of the disc 1500b with the shaft 99, a contact strip on this disc closes circuit between the blades 1511a and 1511 and thereupon circuit is extended through the conductor 1512, Figs. 54 and 55, to the terminal block 1014 and from this terminal block the circuit is extended, in the manner described above, to effect energization of the solenoid 170, Fig. 62.

It is also to be noted that in the present cycle of operation by reason of the fact that the main platen MP is not operated, a pin as 1291 is not pushed, Fig. 62, and it will be understood that advancing of the hub 1283 in reciprocations of the rocker 150 is effected at a time in the cycle of operation subsequent to that at which the Bowden cable 1280 pushes or does not push a pin 1291. Thus the pin 1291 which is not pushed in the ensuing cycle of operation is advanced one step in this cycle of operation. In the next reciprocation of the carrier bars 121 and 122 in the succeeding cycle of operation, this unpushed pin 1291 is moved into position to cooperate with and close the switch 1292. Inasmuch as this is the reciprocation of the carrier bars 121 and 122 in which the printing and control device bearing the tab TB, as aforesaid, is disposed in station V, no impression will be made therefrom because the switch 1292 is closed in the cycle of operation

126

at a time therein prior to the time the particular printing and control device comes to rest in station V. Therefore, the solenoid 327, which is energized upon closing of the switch 1292, will be energized to retract the printing face 301 from effective position. Hence irrespective of whether or not the platen PP is operated in this particular cycle of operation no impression will be made from the printing and control device at station V.

In the course of rotation of the shaft 117 thus effected, the Bowden cable restoring solenoid 472, Fig. 37A, is energized and, as stated, the printing and control devices are advanced but all other operations in the machine, save those above described, are suspended. If the printing and control device succeeding that bearing a tab as TB, as aforesaid, does not bear such a tab, a normal automatic operating cycle follows the present cycle and this is effected in the manner described hereinabove, and as specifically shown in the timing chart of Fig. 63A of the drawings.

Operation to pass a printing and control device through the machine without having impressions made therefrom following an operation in which a printing and control device is passed through the machine without having impressions made therefrom

In an instance where a printing and control device bearing a tab TB passes through the machine immediately behind another printing and control device bearing a tab TB, the machine is operated in the manner described hereinabove with reference to the operation in which a printing and control device bearing such a tab is passed through the machine, and the timing of the various operative elements of the machine in such a cycle is shown in Fig. 63 of the drawings. It is to be noted, however, that in this cycle of operation even though the platen PP will be operated, no impression will be made at station V, for it will be recognized that the printing and control device D to which the preceding or first skip cycle pertained will be located at station IV at the time when the platen PP is operated. Moreover, it will be clear that when the printing and control device D to which the first skip cycle pertained is advanced to station V during the second skip cycle, as indicated in Fig. 63, the related and unpushed pin 1291 will have been advanced two steps by the time such a printing and control device attains station V and will therefore have been effective to energize the solenoid 327 to effect retraction of the printing face 301 of the platen PP to its ineffective position when the platen PP is operated in the next cycle of operation, as indicated in Fig. 63. In all other respects, a cycle of operation of this character corresponds to that described hereinabove with reference to a cycle of operation in which a printing and control device bearing a tab TB is passed through the machine.

Operation in which a page total is printed

As has been explained, in the present machine, a page total PTT is printed on the web W at what is to be the bottom of each proof sheet as PS1, Fig. 5, and, as has been explained, such a total is printed after twenty items, that is to say, after twenty impressions of related changeable data A and variable data V1 and V2 have been printed on the web W. This operation of printing such a page total on the web W, under control of the accumulator AC-PT in the manner hereinabove described, is effected automatically in

the course of operation of the machine, in the manner to be described, unless a ledger total is to be printed, in which event operation of the means normally effective to bring about printing of a page total is suspended in which event, the operation of printing a page total is effected under control of other means, as will be explained hereinafter. The timing of the various operative elements of the machine in a normal page total cycle is shown in Fig. 64.

With respect to the timing chart of Fig. 64, as well as the other timing charts that relate to the total taking cycles of the machine, it should be observed that such cycles of operation are much shorter than the normal cycles of operation of the machine. In such total cycles, however, the unit 600 is operated through its complete cycle, and to attain consistency in the various illustrations of the timing of the unit 600, the various total taking cycles have been shown on the same scale or unit of time that has been employed in the illustration of the normal machine cycles.

The operation of printing a page total PTT on the web W is initiated under control of the counting device 1600, Figs. 52 and 55, included in the pager and proofer machine PM and which embodies the pawls as 948 and 954, Fig. 52A. In the manner explained hereinabove, when twenty items have been printed on the web W, means included in the aforesaid counting device 1600 are effective to so actuate the pawl 948 as to close the switches 946 and 947, Figs. 55 and 52A, at substantially the time shown in Fig. 64.

Upon closure of the switch 947, Fig. 64, circuit is extended from battery B15, Fig. 55, through conductor 1601 to blade 1602 of switch 947, a contact on which is engaged at this time with a contact on the blade 1603 of this switch. Hence from the blade 1603 circuit is extended through the conductor 1604 to the normal closed switch 1605. From the switch 1605 circuit is continued through conductor 1606, Figs. 55, 56 and 57, to terminal block 1430 and thence through conductor 1431 to one end of the winding in relay 1195 and thence to ground from the other end of this winding in the manner explained hereinabove. Such energization of the relay 1195 breaks the above described stick circuit for the relay 1190, Fig. 64, which thereupon deenergizes and breaks the circuit to the solenoid 831 of the main clutch MC so as to suspend operation of the main timing switch shaft 802 in this operation in which a total PTT is to be printed.

As has been explained hereinabove, the pawl 948 is initially effective to close both the switches 946 and 947 but subsequently it is effective to close only the switch 946 for the reason that closure of the switch 947 should be effective only in the present cycle of operation and the circuit established through this switch should be opened when the succeeding cycle of operation is to be initiated. The pawl 948, however, remains in switch closing position until the succeeding cycle of operation is in progress.

Therefore, closure of the switch 946 is effective to extend circuit from battery B15, Fig. 55, through the conductor 1601 to the blade 1607 of the switch 946 and since a contact on this blade is at this time engaged with a contact on the blade 1608 of this switch, circuit is continued from the blade 1608 through the conductor 1609, Figs. 55 and 54, to a blade 1610 associated with the switch disc 1026n of the switch discs 1026 included on the shaft 802. At the time circuit is thus extended

to the blade 1610 the shaft 802 will be completing a revolution and this is effective to bring a contact strip on the switch disc 1026n into position to close circuit between the blade 1610 and the other blade 1611 that is associated therewith and by the time the shaft 802 comes to rest the circuit so closed will be opened for by this time the contact strip will have moved from circuit closing relation with the blades 1610 and 1611. However, the circuit thus extended to the blade 1611 is extended therefrom through conductor 1612, Figs. 54, 55 and 57, to the terminal strip 1613, Fig. 57. The circuit thus extended to terminal strip 1613 is effective to bring about energization of the solenoid 1615, Figs. 57, 50 and 51, included in the switching or timing unit 987 and to this end circuit is extended from the terminal strip 1613 through the conductor 1614, the winding of the solenoid 1615, and thence through conductor 1616, Figs. 57 and 55, through the normally closed switch 1617 to ground through the conductor 1618.

By referring to Fig. 51 it will be seen that a pawl 1619 carried by the armature 1620 of the solenoid 1615 is normally effective to restrain the disc 1621 of a slip clutch against rotation and in this respect it is to be noted that the other disc 1622 of this clutch is constantly driven so long as the main drive shaft 90 is in operation. Thus the disc 1622 is in the form of a gear and the teeth thereof are meshed with a pinion 1623 which, in turn, meshes with a pinion 1624 fast on the shaft 1625 journaled in the housing of the unit 987. A pulley 1626 is fast on the shaft 1625 and an endless belt 1627, Figs. 50 and 9, is passed about this pulley and a pulley 1628 fast on the main drive shaft 90.

When the pawl 1619 is moved from restraining position with respect to the disc 1621, upon energization of the solenoid 1615 in the manner just explained, the shaft 1629 on which this disc is fast is set in rotation to thereby rotate the switch discs as 1174, Figs. 50 and 57, fast thereto and it is these switch discs that are effective to close circuits that bring about the printing of a page total as PTT on the web W.

Thus a contact strip on the switch disc 1174a moves into circuit closing relation with the blades 1631 and 1632 associated therewith shortly after the shaft 1629 is set in operation. Thereupon circuit is extended from battery B16, Fig. 57, through conductor 1673, terminal 1674, conductor 1630, blade 1631, blade 1632, to terminal 1633, and thence through conductor 1634, Figs. 57 and 55, to terminal 1635, and thence through conductor 1636 to one end of the winding of the solenoid 746, Figs. 55 and 33, and then to ground through conductor 1637.

The solenoid 746 is effective in the manner explained hereinabove to position the cam plates as 757 in the position required for the taking of a page total since at this time the shroud 755, Fig. 32B, is disposed to prevent the pawl 752 from engaging the tooth 756.

Upon energization of the solenoid 746, Fig. 33, the link 748 is moved downwardly, as described hereinabove, whereupon the adjustment screw 764 effects closure of the switch 765, Figs. 33 and 55. Closure of the switch 765 extends circuit from battery B17, Fig. 55, through conductor 1638 to closed switch 765 and conductor 1639, to the terminal strip 1260. The circuit thus extended to terminal strip 1260 is extended through the conductor 1261 to the winding of the solenoid 577 and to ground, in the manner described hereinabove, from the other end of the winding of this

solenoid. Thereupon the solenoid 577 energizes to set the cam shaft 560 of the printing unit 600 in operation, Fig. 64.

In the ensuing operation of cam shaft 560, the accumulator wheels 705 of the accumulator AC-PT are effective, in the manner described hereinabove, to set up the type segments TS2 to dispose type characters TC/ from which the total represented by the set position of these accumulator wheels may be printed and then the platen PP is set in operation to print this total on the web W. Thereafter, as explained hereinabove, the total so printed is entered into the accumulator AC-LT and AC-GT. In this operation, in the manner described hereinabove, the switch disc 1263b, Fig. 55, on the cam shaft 560 is effective to close the circuit which brings about operation of the platen PP as described hereinabove.

Inasmuch as a printing unit 600 is set in operation when a total PTT is to be printed on the web W and since this total will be printed on the web in cooperation with the printing face 302 of the platen PP it is necessary that the web W be advanced as an incident to this cycle of operation. This will move the portion of the web W so printed into alignment with a printing and control device at station V. However, in the operation which succeeds an operation in which a total PTT is printed, no impression is to be made from the printing and control device disposed at station V for the necessary impression of changeable data A from this printing and control device will be effected in the operation in which the total PTT is printed on the web and since the printing face 301 of the platen PP remains in its effective position in the operation in which the total PTT is printed this is effected. However, in the succeeding cycle of operation the printing face 301 of the platen PP is to be rendered ineffective so that changeable data A will not be printed in association with the total PTT for the reason that this total is not related to any particular changeable data A as are variable data V1 and V2. Therefore in the cycle of operation which succeeds an operation in which a total PTT is printed the printing face 301 of the platen PP is disposed in its ineffective position if the platen PP is rendered effective in such succeeding cycle of operation.

To this end, in the cycle of operation in which a total PTT is printed, a circuit is established to the solenoid 327 and this circuit is closed in the succeeding cycle of operation. Such energization of the solenoid 327 causes the printing face 301 to be disposed in ineffective position, as explained above. Hence, when in the course of operation of the pager and proofer mechanism PM to advance the web W in the cycle of operation in which a page total PTT is printed, the switch 953, Figs. 55 and 52A, is closed by the pawl 954, Fig. 64. In this respect, the pager and proofer mechanism PM is rendered effective in this operation, as in all other operations of the printing unit 600 under control of the switch disc 1263b operated from the cam shaft 560 of the unit 600. The pawl 954 which is effective to close the switch 953 is included in the counting mechanism 1600 and is so arranged therein that it closes the switch 953 near the end of a cycle of operation in which a total PTT is printed, Fig. 64, and this pawl maintains this switch closed until the pager and proofer mechanism PM is rendered operative in a succeeding cycle of operation.

Thus, in a cycle of operation succeeding that in which a total PTT is printed the switch 953 is closed. Closure of the switch 953 extends circuit from battery B15, Fig. 55, through conductor 1601, conductor 1645, through closed switch 953 and conductor 1646 to terminal strip 1299. The circuit thus extended to terminal strip 1299 is extended through conductor 1300, Figs. 55 and 54, to the winding of solenoid 327 and then to ground at 1301. Hence, near the end of a cycle of operation in which a page total PTT is printed the solenoid 327 is energized and this solenoid remains energized so that in a succeeding cycle of operation in which the platen PP is operated, the means under control of this solenoid will be effective to dispose the printing face 301 of this platen in its ineffective position, in the manner described hereinabove. However, in the cycle of operation in which the platen PP is so operated, the pager and proofer mechanism PM is also operated and therefore the pawl 954 is moved into a position wherein it is ineffective to close the switch 953 and this pawl does not again become effective until a page total is to be printed.

It is to be noted that the operation of printing a page total, which has just been described, will only be effected in an instance where a printing and control device is disposed at station V that is to have an impression made therefrom.

Near the end of a cycle of operation in which a page total PTT is printed on the web W, the switch 1174b, Figs. 50 and 57, in the switching unit 987 is effective to close circuit between the blades 1175 and 1173 associated therewith. In this instance circuit will be extended to the terminal 1177, Fig. 56, from battery B5, Fig. 56, in the manner hereinabove described. Therefore from terminal 1177 circuit is extended through conductor 1642, Figs. 57 and 56, to blade 1173, and at this time a contact strip on the switch disc 1174b will be closing circuit to the blade 1175 and therefore from this blade circuit is extended through conductor 1643, Figs. 57 and 56, to terminal 1185, and thereupon the relay 1190 is energized, Fig. 64, to establish a circuit which may be rendered effective in the succeeding cycle of operation to bring about energization of the solenoid 831 of the main clutch MC if in the succeeding cycle of operation the timing shaft 802 is to be operated.

Inasmuch as the cam shaft 802 is not operated in the cycle of operation in which a total as PTT is printed on the web W those operations which proceed under control thereof, in the manner described hereinabove, are suspended in this cycle of operation and therefore only those operations just described which effect the printing of a total as PTT are brought about in such a cycle of operation.

Operation in which a page total and a ledger total are printed

By referring to Fig. 6 it will be seen that there are instances where both a page total PTT and a ledger total LT are printed on a proof sheet. It has been explained hereinabove that the operation for printing a ledger total as LT is initiated under control of a special tab as TBS, Fig. 5, on a printing and control device D. It is also to be noted that the printing of a page total PTT at the time when a ledger total LT is to be printed is not effected under control of the counting device 1600 but is effected under control of mechanism rendered operative to bring about the printing of a ledger total LT, and the timing of

the various operative elements of the machine in initiating and carrying out such a ledger total operation is illustrated in Figs. 65 and 66 of the drawings.

In a normal cycle of operation in which a tab TBS closes the switch 988 circuit is extended from battery B2, Fig. 55, conductor 1023 to blade 1670 associated with a switch disc 1020g, Figs. 55 and 10, operated from the shaft 117 and in the course of a rotation of the shaft 117 when the switch 988 is closed, Fig. 65, a contact strip on this switch disc closes circuit to blade 1671 associated therewith. Circuit is extended from the blade 1671 through a conductor 1672, Figs. 55 and 57, through the now closed switch 988, conductor 1673a, Figs. 57 and 56, through terminal 1683, conductor 1684, to one end of the winding of the relay 1170, and from the other end of this winding circuit is extended to ground through conductor 1434. It will therefore be seen that closure of the switch 988 is effected to energize the relay 1170, Fig. 65.

Upon energization of the relay 1170 a stick circuit is established therefor. To this end circuit is extended from battery B16, Fig. 57, through conductor 1673 to a terminal 1674 and thence through conductor 1675 to a blade 1676 associated with the switch disc 1677a on the shaft 991 of the switching unit 987, Fig. 49. At the time the switch 988 is closed a contact strip on the switch disc 1677a will be closing circuit between the blade 1676 and the blade 1678, associated therewith. Hence circuit is extended from blade 1678 through conductor 1679, Figs. 57 and 56, to the contact 1680 of the relay 1170 which, by reason of the fact that this relay will at this time be energized, will be in engagement with the contact 1681 of this relay. Thus, the stick circuit for the relay 1170 is completed from the contact 1681 through conductor 1682, terminal 1683 and conductor 1684, through the winding of the relay 1170, to ground through conductor 1434 and therefore the relay 1170 remains energized until this stick circuit is broken in the manner explained hereinafter.

Energization of the relay 1170 is also effective to engage the contacts 1685 and 1686 thereof and this is effective to close circuit to the solenoid 1615, Figs. 51 and 57, in the switching unit 987. In this instance circuit is extended from battery B18, Fig. 56, through conductor 1689, contact 1685, contact 1686, conductor 1690, Figs. 56, 57 and 55, to a blade 1691 associated with the switch disc 1020h on the shaft 117. At the time circuit is thus extended to the blade 1691 a contact strip on this switch disc will be closing circuit to the blade 1692 associated therewith and from this blade circuit is extended through the conductor 1693, Figs. 55 and 57, to terminal strip 1613, to thereupon energize the solenoid 1615 of the switching unit 987, whereupon, in the manner explained hereinabove, the shaft 1629 of the switching unit 987 is set in operation. Thereupon under control of the switch disc 1174a a page total PTT is printed on the web W in the manner explained hereinabove.

It is to be noted that when a page total PTT is printed in an operation in which a ledger total LT is also to be printed, circuit is not closed to the relay 1190 in the manner explained hereinabove with reference to the taking of a page total PTT in the normal way since automatic operation of the machine is not to succeed the taking of a page total PTT in an operation where a ledger total LT is also to be printed. There-

fore the contacts 1169 and 1161, Fig. 56, on the relay 1170 are opened upon energization of this relay in the manner explained hereinabove when a total LT is to be printed and it is this that breaks circuit to the relay 1190, Fig. 65, that would otherwise be closed in the course of taking the page total PTT.

It will be understood that at this time the switch discs 1174 on the shaft 1629 of the switching unit 987 are in operation and in the course of rotation of these switch discs a contact strip on the switch disc 1174c is effective to close a circuit to energize the solenoid 1688 of the switching unit 987. This circuit is not closed in the course of taking a page total PTT in the normal way because when the relay 1170 is deenergized, as it is in a normal operation for printing a page total PTT, the contact 1700 is disengaged from the contact 1699, wherefore circuit cannot be extended to the winding of the solenoid 1688.

However, when the contact strip on the switch disc 1174c is to be effective to close a circuit, as it is in the present instance, circuit is extended from battery B16, Fig. 57, through conductor 1673, to terminal 1674 and thence through blade 1696 associated with the switch disc 1174c, through the contact strip on this disc, to the blade 1697 associated therewith and thence through conductor 1698, Figs. 57 and 56, to the contact 1699 of the relay 1170 which at this time, because this relay is energized, is engaged with the contact 1700 thereof. Hence, from the contact 1700 circuit is continued through the conductor 1701, Figs. 56 and 57, to one end of the winding of solenoid 1688 and thence through conductor 1702 circuit is extended to conductor 1616 and thereafter to ground in the manner explained hereinabove and thereupon the solenoid 1688 is energized, Fig. 66.

Energization of the solenoid 1688 effects engagement of a slip clutch included in the switching unit 987 and embodying a disc 1704, Fig. 51. Upon energization of the solenoid 1688 the disc 1704 engages the disc 1705 which is in the form of a gear that has the teeth thereof meshed with the pinion 1624 and thereupon the shaft 991 of the switching unit 987 is set in operation to thereby set the switch discs 1677 thereon in operation.

When the shaft 991 is thus set in operation the cam 1706 thereon acts on the cam follower 1707 associated therewith to pivot the lever 1708 downwardly. The Bowden cable 992 described hereinabove is connected to this lever and upon such downward movement of this lever, this cable is effective to so move the shroud 755, Fig. 32B, that the tooth 756 is disclosed to the pawl 752 at the time indicated in Fig. 66.

Consequently when the solenoid 746, Fig. 33, is energized in a manner now to be explained the cam plates 757 are disposed in such positions that the rockers 722 in the various accumulators are disposed in the positions into which they are to be moved when a ledger total is to be taken, this having been described hereinabove.

In this instance the energization of the solenoid 746 is effected through a circuit that is extended from battery B16, Fig. 57, through conductor 1673, terminal 1674, conductor 1675, to a blade 1710 associated with the switch disc 1677b on the shaft 991 of the switching unit 987. At the time this occurs a contact strip on the switch disc 1677b will be closing circuit between the aforesaid blade 1710 and the other blade 1711 associated therewith and from this blade the cir-

cuit is extended through a conductor 1712, Fig. 57, to terminal 1633, and thus through a conductor 1634 in the manner described hereinabove to effect energization of the solenoid 746. Such energization of the solenoid 746 is effective to close the switch 765, Figs. 33 and 55, to thereupon set the cam shaft 560 of the unit 600 in operation, Fig. 66, in the manner described hereinabove in the operation in which a page total PTT is printed on the web W in a normal manner.

It will be recollected that the stick circuit for the relay 1170, Fig. 56, was established through blades 1676 and 1678, Fig. 57, associated with a switch disc 1677a on the shaft 991 of the switching unit 987. Therefore after the solenoid 746 has been energized, in the manner just described, to set the printing unit 600 in operation so as to thereby bring about printing of a ledger total LT on a proof sheet as PS2, the contact strip on the switch disc 1677a moves out of circuit closing position with respect to the blades 1676 and 1678 and thereupon the stick circuit to the relay 1170 is broken.

It is essential in the operation of printing a ledger total that the printing face 301 of the platen PP be disposed in ineffective position, Fig. 66, and to this end, at the time platen PP is set in operation to print a ledger total LT on the web W, circuit is closed to the solenoid 327, Figs. 54 and 24. In this instance circuit is extended from battery B16, Fig. 57, through conductor 1673, terminal 1674, conductor 1675, to switch blade 1730 associated with switch disc 1677c on the shaft 991 of the unit 987. A contact strip on this switch disc is effective at this time to close circuit between the blades 1730 and 1731 associated therewith. Hence from the blade 1731 circuit is extended through the conductor 1732, Figs. 57 and 55, to the terminal strip 1299 and thence through conductor 1300 energization of the solenoid 327 is effected. The contact strip on the switch disc 1677c disengages the blades 1730 and 1731 prior to completion of the ensuing operation and therefore the solenoid 327 is deenergized before the completion of this cycle of operation.

Near the end of this cycle of operation, Fig. 66, the cam 1106 effects restoration of the shroud 755 in position to prevent the pawl 752 from engaging the tooth 756 until a ledger total LT is again to be printed.

Moreover, as explained hereinabove, the counting device 1600 should be restored to its zero position at the end of an operation in which a ledger total LT is printed so as to insure that a page total as PTT will not be printed until after twenty items have been printed on the web W. It is also to be noted that unlike an operation in which a page total PTT is printed circuit is not reestablished to the solenoid 831, Fig. 54, in an operation in which a ledger total is printed. Therefore, in order to set the machine in operation subsequent to the taking of a ledger total it is necessary to push the button 1131, Fig. 54, of the start-stop switch 1135 to again set the machine in operation. It will also be understood that, as in the case of taking a page total PTT, the main switch shaft 802 does not rotate, Fig. 66, and therefore in the printing of a page total PTT and a ledger total LT those operative functions of the machine which proceed under control of switch discs on this shaft are suspended.

Operation in which a grand total is taken

When a grand total GT is to be printed on a proof sheet as PS3, Fig. 7, this will usually follow

the printing of page and ledger totals as shown in Fig. 7 where page total PTT and a ledger total LT are printed, in the manner above described, to appear before the grand total GT that is printed on the proof sheet PS3. Since the printing of a grand total in this manner will follow the printing of page and ledger, in an operation such as that just described, the accumulators AC-PT and AC-LT will be zeroized.

- 10 In an operation where a grand total is to be printed, the crank 993, Fig. 25, is grasped and the shaft 750 is rotated, as described hereinabove, into such position that the shoulder 981, Fig. 33, seats on the tooth 980 to thereby retain the shaft 750, and the cam plates as 757 thereon, in the hereinabove described positions into which these parts are moved when a grand total is to be read out of the accumulator AC-GT. The rocker 722 of the accumulator AC-GT is disposed, in such an instance, in position to have the gear segment 726 thereon mesh with teeth on the rack 728 for the purpose explained above.

After the parts have been so positioned, the manually operable switch key 1890, Figs. 1 and 25, is pressed to engage a contact on the blade 1801 with a contact on the blade 1802. Thereupon circuit is extended from battery B26, Fig. 55, through conductor 1803, blade 1801, blade 1802 to terminal 1635, and thence through conductor 1638 to one end of the winding of the solenoid 746, Figs. 33 and 55, and thereafter to ground through the conductor 1631. Thereupon the solenoid 746 is energized with the effect hereinabove described, and in this instance when the cam shaft 560 of the printing unit 600 is set in operation by closure of the switch 765, incidental to the energization of the solenoid 746 as explained hereinabove, a grand total GT is printed on the web W in a position like that shown in Fig. 7.

In the operation of printing a grand total as well as in the operations of printing a page total PTT or a ledger total LT, a total of both the variable data as V2, the number of shares of stock, in this instance, owned by the persons or the like to whom the printing and control devices D pertain, is printed as well as a total of the amount of money for which the checks as S have been prepared to be payable. This amount of money is the product of the number of shares of stock and the reoccurring factor included in the templets PT and the templet-gangs TG. Thus, when a total is printed, a cross check is afforded for by multiplying the number of shares of stock which appear in the total by the aforesaid reoccurring factor, the product thus attained should be equal to the amount of money for which the checks S have been payable, which is represented by the total accumulated of the variable data V1 that have been printed. Therefore, a check on the automatic operation of the machine is afforded.

Operation to sever the web

It has been explained hereinabove that, after twenty items have been printed on the web W and a page total PTT has been printed to follow such items, in the manner explained hereinabove, the web W advances to a severing knife 915. It has also been explained that severance of the web to thereby provide a proof sheet as PS1 does not immediately follow the printing of a page total PTT, but that the web is advanced, from the position at which the page total PTT is printed thereon, to the aforesaid severing knife. When the

portion of the web suitably spaced beneath the page total PTT is aligned with the knife, the knife is operated, under control of the pin 942 in the counting mechanism 1600, the pin 942 at this time moving into position to close the switch 943, Figs. 52A and 55. Closure of the switch 943 conditions the circuit that is closed under control of the switch disc 1263b, Fig. 55, when the pager and proofer mechanism PM is next set in operation. Circuit in this instance is extended from battery B8, Fig. 55, through conductor 1264, blade 1306, contact strip on the disc 1263b, blade 1307, conductor 1308 to a terminal 1804 therein. The circuit thus extended to the terminal 1804 is continued through the conductor 1805, now closed switch 943 and conductor 1806 to one end of the winding of the solenoid 935, Fig. 53, which, through the intermediary of a one-revolution clutch 934, sets the shaft 921 in operation to thereby cause the knife 915 to sever the web W as aforesaid, circuit from the other end of the winding of the solenoid 935, in this instance being completed to ground through the conductor 1309, Fig. 55.

MODIFIED FEEDING MEANS FOR PRINTING AND CONTROL DEVICES

In this instance, where the keys 813 and 820, Figs. 46 and 47, are arranged in the manner shown in Fig. 47 to condition the machine to be operated in a consecutive manner, as described hereinabove, variable data VI will be printed on the web W by the platen PP in a cycle of operation succeeding that in which the related data V are printed. In such instances it is necessary that the printing and control device which is disposed at station III, when the variable data V are so printed, be advanced to station V near the end of this cycle of operation in which these data V are printed so that when the web W is indexed, in the manner herein above described, so as to bring the portion thereof whereat the variable data V have been printed into the position to receive an impression of related changeable data A in alignment therewith, the printing and control device from which these data A are to be printed will be in station V, so that this will be done.

In the instance where the machine is arranged for consecutive operation, the main switch shaft 802 makes but a single revolution for each revolution of the timing drive shaft 104. In such an instance, the switch disc 1026c is modified so as to be effective to close circuit to the solenoid 170 only once in each cycle of operation of the machine, rather than twice, as is done when the machine is arranged for duplicate operation, as has been explained hereinabove. Moreover, the switch disc 1026f is so modified that it closes circuit to the solenoid 271 but twice when the machine is arranged for consecutive operation and other controls are also modified, as for example, in consecutive operation there is no need to energize the solenoid 831 at an intermediate time in the rotation of the shaft 104 which makes one but not two rotations when the machine is in condition for consecutive operation. Therefore, since the switch disc 1026c will only energize the solenoid 170 once in each cycle of operation, the shaft 117 will make but a single revolution and consequently the carrier bars 121 and 122 will make but a single reciprocation.

Moreover, in such an instance, circuit to the solenoid 208, Fig. 20, is broken. Therefore the spring 193, Fig. 22, remains in such position that the free ends 192 thereof will cooperate with

fingers as 191 in every reciprocation of the carrier bars. Hence none of the printing and control device advancing pawls is rendered ineffective to advance printing and control devices.

Therefore, when the machine is arranged for consecutive operation, in every reciprocation of the carrier bars 121 and 122, a printing and control device is advanced from station I to station II and another is advanced from station II to station III once the machine is functioning automatically. In such an instance, however, the printing and control device which is disposed at station III must be advanced into station V at once. In these circumstances, the printing and control device does not come to rest in a station corresponding to that identified as IV hereinabove. Furthermore, it is necessary in such instance, since the aforesaid spacing between stations III and V will remain unchanged, to advance the printing and control device through a distance materially greater than the distance the carrier bars 121 and 122 move in the forward stroke of the reciprocation thereof. However, to avoid reciprocating the carrier bars through a very long stroke, the aforesaid stroke, which is sufficient to advance a printing and control device from station II to station III, is retained but the sections of the carrier bars that are effective to advance a printing and control device from station III to station V and from station V to the discharge chute 241 are disconnected from the portion of the carrier bars that advance the devices between the other stations. These front sections of the carrier bars, that are so separated from the rear sections thereof, are operated in such a way that they travel through a distance sufficient to advance a printing and control device from station III to station V even though the rear sections of the carrier bars move only through a distance such as hereinabove described.

Therefore, resort is had to a modified arrangement of the carrier bars, such as that which is shown in Figs. 58 to 60. This arrangement is such that the same actuating mechanism, including the rocker 150, Fig. 10, may be utilized to impart reciprocatory movement to carrier bars. Hence, in the modified form of my invention shown in Figs. 58 to 60, many of the structural elements retain the exact form employed in the construction shown, for example, in Figs. 14 and 15. Where there is such exact correspondence in form the same reference numerals are employed in Figs. 58 to 60 were used hereinabove. In other instances where there are changes of form, the suffix "m" will be employed in Figs. 58 to 60 in connection with the reference numerals used in Figs. 14 and 15.

Referring particularly to Figs. 58 to 60, it will be observed that carrier bars 121mr and 122mr are mounted between the side plates 123 and 124 in substantially the same manner as in Figs. 14 and 15, there being a bracket structure 128m therebetween to receive the slide block 155 of the actuating mechanism. The rear portions of the two carrier bars 121mr and 122mr are constructed and arranged in the same manner as in the mechanism shown in Figs. 14 and 15, and the pawls are arranged thereon in the same relation and with the same spacing, with the exception, however, that the pawls which advance printing and control devices from station I to station II are in this instance effective in each cycle of operation of the carrier bars. The forward end portions of the carrier bars 121mr and 122mr are cut away at their upper edges to pro-

vide an upwardly facing surface 955 along which other carrier bar means may slide at a rate which is different than the rate of movement of the carrier bars 121mr and 122mr. On the surface 955 of the carrier bar 121mr, a relatively short carrier bar 121mf is mounted, and a similar relatively short carrier bar 122mf is mounted on the upwardly facing surface 955 of the carrier bar 122mr. The carrier bars 121mf and 122mf have pairs of pawls 956 and 957 mounted thereon so that when these carrier bars are moved to the rear extent of their stroke, the pawls 956 will be located rearwardly of a printing and control device positioned at printing station III. When movement of the carrier bars 121mf and 122mf is reversed, the pawls 956 engage and advance the printing and control device from station III in a forward direction. As this movement progresses the pawls 957 engage the rear edge of the printing and control device located at station V, thereby to advance this printing and control device to the collecting means. At the completion of the forward stroke of the forward carrier bars 121mf and 122mf the printing device which has been advanced from station III by the pawls 956 is located at printing station V.

Means is provided whereby the actuating means which includes the slide block 155 are effective to move the carrier bars 121mf and 122mf at a speed which is greater than the speed of movement of the rear carrier bars 121mr and 122mr, and since the distance between the stations III and V is twice the distance between stations II and III, the present means for accomplishing this result are arranged to move the front carrier bars at twice the speed of movement of the rear carrier bars. In accomplishing this result a geared interconnection is provided between the bracket 128m and the front carrier bars. Thus each of the two front carrier bars has an inwardly facing rack 958 formed thereon so as to mesh with one side of an adjacent pinion 959 mounted on the vertical axis 960 on a cross bar portion 961 of the bracket 128m. It will be understood that two such pinions 959 are provided as shown in Fig. 58 of the drawings, and these pinions are spaced apart so as to mesh respectively with rack portions 962 and 963 of a double edge rack 964. The double edged rack 964 is stationarily mounted so as to extend between the two anvils 131 and 132, one end of the rack being connected to the anvil 131 by screws 965 while the other end of the rack is connected to the anvil 132 by screws 966. Thus it will be evident that as the bracket 128m is moved by the actuating means, the two pinions 959 will roll along the edges of the rack 964. The movement of the pinions longitudinally of the guideway G will, of course, be at the same rate as the movement of the bracket 128m, but the rotative movement of the two pinions 959 will impart movement to the racks 958 and hence to the front carrier bars, at a speed which is double the speed of movement of the bracket 128m. As a result it will be clear that while the rear carrier bars are moving through a relatively short stroke, the front carrier bars will move through a relatively long stroke, and the printing and control device from station III will be fed from station III to station V in but a single operation of the actuating means. It will be evident that gearing similar to the gearing 958-959-964 might be readily modified through the provision of two intermediate gears on each axis 960 so

as to obtain a different ratio between the speeds of movement of the front and rear carrier bars, the two interconnected pinions in such an instance being of different diameters.

SUMMARY

It will be manifest from the foregoing description that when the machine is arranged for duplicate operation, the printing and control devices will so advance therethrough that when a printing and control device attains station II it is sensed to condition the control for the multiplying mechanism M that is afforded by the positioning of the pins as 442, Fig. 37A, in the ends of the Bowden cables 357, that are pushed by the pins 351 in the detecting head 352 under control of the coded perforations 85 in the printing and control device then disposed at station II. Moreover, as one of the final steps in the cycle of operation in which the control for the multiplying mechanism is so set up, the printing and control device, under control of which this is effected, is advanced from station II to station III.

In the succeeding cycle of operation the multiplying mechanism M is set in operation and thereupon changeable data A are printed on a check S, by operation of the main platen MP, from the aforesaid printing and control device, and by reason of the operation of the multiplying mechanism M in this cycle the variable data V are printed on the check S and also on the web W. Furthermore, as soon as the changeable data A are printed on the check S and while the variable data are being printed, the printing and control device that was at station III is, in the first of the two reciprocations of the carrier bars 121 and 122, advanced to station IV and then in the second of the reciprocations of the carrier bars, this printing and control device is disposed at station V.

The variable data V printed on the web W in such an instance is printed thereon in such position that when the web W is moved through one step in the step-by-step advancing that is imparted thereto, this impression of the variable data V is located in such position that, when the platen PP is set in operation in the succeeding cycle of operation, changeable data A are printed from this particular printing and control device in association with the variable data V.

Such operation of the machine insures that the variable data A and changeable data V that may be derived from a particular printing and control device are printed on the same check as S, and it also insures that such changeable data A and variable data V appear in related positions on the web W.

Moreover, when the machine is arranged for consecutive operation as explained hereinabove, as in the instance of duplicate operation, a control for the multiplying mechanism M is set up as aforesaid in one cycle of operation and the printing and control device under control of which the control for the multiplying mechanism is so set up is advanced from station II to station III. Hence, when the machine is set in operation in a succeeding cycle of operation and the multiplying mechanism M is set in operation, the main platen MP operates to print changeable data A and variable data V on the check S, and therefore these variable data are derived from the same printing and control device. Moreover, when the machine is arranged for consecutive operation, through the intermediary of a printing and control device advancing means such as that

disclosed in Figs. 58 to 60, the printing and control device thus disposed at station III is advanced therefrom into station V. In consecutive operation, the variable data V are printed on the web W in one cycle of operation and the web is then advanced just as in the case of duplicate operation and also as in duplicate operation, when the platen PP is operated in the succeeding cycle of operation, changeable data A related to the variable data V so printed are printed on the web in relation with the variable data V thereon.

It will therefore be seen that the various instrumentalities in the present machine are so operated under control of and in relation to printing and control devices that both changeable data A and variable data V derived from a particular printing and control device are printed on a particular check as S, and these data are also printed at related positions on the web W.

In order that the foregoing may be brought about, the carrier bars 121 and 122 are operated to make two complete reciprocations in every cycle of operation when the machine is arranged for duplicate operation but, as explained hereinabove, the operation of the printing and control device advancing means on the carrier bars is so controlled that selected of the printing and control devices are advanced in one reciprocation of the carrier bars, while other of the printing and control devices remain at rest and this control is of such nature that all of the printing and control devices in the guideway therefor may be advanced by the carrier bars when so desired.

Moreover, in an instance where the machine is arranged for consecutive operation, the modified arrangement of the carrier bars described hereinabove may be resorted to to enable selected of the printing and control devices to be advanced through a distance materially greater than the distance through which the carrier bars advance in the course of the forward or printing and control device advancing stroke thereof. It will be understood that resort could be had to this modified arrangement for advancing the printing and control devices for purposes other than that described hereinabove for there may well be many instances where it will be desirable to impart material advancing movement to printing and control devices, and resort to an arrangement of this character avoids the necessity of causing the carrier bars to be moved through a reciprocatory stroke greater than that which can be afforded without objectionably increasing the size of the machine.

Moreover, by resort to an arrangement such as that afforded by the plate 770, Fig. 38, which may be operated as a separate instrumentality or as a part of a calculating mechanism, as in the present instance, I am enabled to print the values of the variable data that controls, in the present instance, operation of the calculating mechanism, as explained hereinabove. Moreover, by the use of the novel accumulating arrangement which I have described hereinabove I am enabled to accumulate totals of the data so printed and I am so enabled, by the use of the novel accumulating mechanism described hereinabove, to print the total so accumulated.

With respect to the novel accumulating mechanism, the hereinabove described arrangement thereof is such that this mechanism automatically functions to accumulate totals in selected of the plurality of accumulators included in the machine, and the arrangement is such that the totals so accumulated in selected accumulators

thereof may be read into other of the accumulators as an incident, for example, to printing of a total accumulated in selected of the accumulators. Moreover, while the accumulators may be automatically operated, it will be understood that each or all of the accumulators could be manually operated if so desired, for example, in the manner in which the accumulator from which grand totals are printed, as has been explained hereinabove.

Furthermore, where resort is had to a calculating mechanism, such as the multiplying mechanism M in the present instance, that embodies devices that are set in digit representing amounts, I am enabled by the novel setup devices hereinabove described to set variable settable printing members in such positions as to print the amounts the devices in the calculating mechanism are so set to represent and, if desired and as is done in the present instance, such amounts may also be entered into selected of a plurality of accumulators that may be included in the machine, as has been referred to hereinabove. Moreover, it is to be noted that the novel arrangement to which I have resorted for bringing about the setting up of variable settable type members in the present instance embodies devices, such as the pinions 532 in the present instance, which are constantly operated in a given direction, whereby the necessity of operating such devices in reverse directions to enable entries to be made thereinto and readouts to be taken therefrom is avoided. By resorting to devices which operate in but one direction, I very materially simplify the restoration of such devices, such as would be required, for example, if the devices were required to be operated in opposite directions in order to enable entries to be made thereinto and readouts to be taken therefrom.

It will be understood from the foregoing description that various safety arrangements are afforded to insure proper operation of the machine, and furthermore the operation of various instrumentalities in the machine at the desired and proper times is insured by primarily controlling the operation of such instrumentalities from a single arrangement. However, as has been explained, by reason of the interrelation among certain of the instrumentalities as, for example, the interrelation between the multiplying mechanism M described hereinabove and the printing unit 600, also described hereinabove, I, in some instances, resort to controlling one instrumentality from another so as to thereby insure proper operative interrelation therebetween.

Furthermore, the control arrangement employed in the machine is so arranged as to enable special operations to be effected when and as required as, for example, those which are needed when a supply of printing and control devices are first introduced into the machine and also those which are required, for example, when totals are to be read out from selected of the accumulators and printed.

Many other advantages and novel features of the present invention will be apparent to those skilled in the art and thus while I have shown and described selected embodiments of my invention, it is to be understood that these are capable of variation and modification and I therefore do not wish to be limited to the precise details set forth but desire to avail myself of such changes and alterations as fall within the purview of the following claims:

I claim:

1. In a machine through which devices are sequentially fed to enable operations to be performed in the machine from or under control of said devices, a guideway, a plurality of at least three stations arranged along said guideway and at which operations are to be performed in the machine from or under control of said sequentially fed devices, means including a carrier movable along said guideway for moving said sequentially fed devices progressively from station to station along said guideway, said carrier comprising sections movable relative to each other during movement of said carrier and including motion-multiplying gearing means operatively connected between said sections and operable to move one of said sections and one of said sequentially fed devices carried thereby from one of said stations to and past an intermediate one of said stations to another of said stations beyond said intermediate station while during the same movement of said carrier another section thereof is effective to move another of said sequentially fed devices from one of said stations to the next adjacent one of said stations.

2. In a machine through which devices are sequentially fed to enable operations to be performed in the machine from or under control of said devices, a guideway, a plurality of at least three stations arranged along said guideway and at which operations are to be performed in the machine from or under control of said sequentially fed devices, means including a carrier movable along said guideway for moving said sequentially fed devices progressively from station to station along said guideway, said carrier comprising a pair of sections movable relative to each other during movement of said carrier, a stationary rack mounted longitudinally on said guideway, at least one pinion mounted on one of said sections and meshed with said rack, another rack mounted on the other section and meshed with said pinion and cooperating with the first mentioned rack and said pinion for moving said one of said sections and one of said sequentially fed devices carried thereby from one of said stations to and past an intermediate one of said stations to another of said stations beyond said intermediate station while during the same movement of said carrier first section thereof is effective to move others of said devices from their respective stations to the next succeeding stations adjacent thereto.

3. In a machine through which devices are sequentially fed to enable operations to be performed in the machine from or under control thereof, a guideway, a plurality of at least three stations arranged along said guideway and at which operations are to be performed in the machine from or under control of said sequentially fed devices, means including a carrier movable along said guideway for moving said sequentially fed devices progressively from station to station along said guideway, said carrier comprising the front section and a rear section movable relative to each other during movement of said carrier, means including a pair of racks mounted respectively on said guideway and on said front section so as to extend longitudinally thereof, at least one pinion mounted on said rear section and engaging both of said racks, said racks and said pinion cooperating to transmit motion from one of said sections to the other of said sections to move said front carrier through a greater distance than the distance through which said rear section is moved

during the same advancing movement of said carrier so that said front section of said carrier is enabled to move one of said sequentially fed devices from one of said stations through and past an intermediate one of said stations and to a station therebeyond without stopping said one sequentially fed device at said intermediate station while, during the same movement of said carrier, others of said sequentially fed devices are moved by said carrier from their respective stations to the next succeeding stations adjacent thereto.

4. In a machine through which devices are sequentially fed to enable operations to be performed in the machine from or under control thereof, a guideway, a plurality of at least three stations arranged along said guideway and at which operations are to be performed in the machine from or under control of said sequentially fed devices, means including a carrier movable along said guideway through advancing movements for moving said sequentially fed devices progressively from station to station along said guideway, said carrier comprising a front section and a rear section movable relative to each other during movement of said carrier, means for actuating one of said sections to reciprocate the same and means including a rack and pinion mechanism mounted within said guideway and in part on said guideway and in part on each of said sections and cooperating with said sections said front section moves through a greater distance than the distance through which said rear section is moved during the same advancing movement of said carrier so that said front section of said carrier is enabled to move one of said sequentially fed devices from one of said stations through and past an intermediate one of said stations and to a station therebeyond without stopping said one sequentially fed device at said intermediate station while, during the same movement of said carrier, others of said sequentially fed devices are moved by said carrier from their respective stations to the next succeeding stations adjacent thereto.

5. In a machine through which devices are sequentially fed to enable operations to be performed in the machine from or under the control of said devices, a guideway along which said devices are sequentially fed, a plurality of stations arranged at spaced intervals along said guideway and at which operations are to be performed from or under control of said devices, a carrier movable along said guideway, a plurality of members movably mounted upon said carrier at spaced intervals thereon for movement into and out of position to engage said sequentially fed devices for movement through a cycle of operation along said guideway from station to station, means cooperating with said carrier at a predetermined time during a cycle of operation of said carrier for moving said members out of position to engage said sequentially fed devices for movement along said guideway, other means cooperating with said carrier at another and different time in a cycle of operation of said carrier for moving said members into position to engage said sequentially fed devices for movement along said guideway, and means under control of operations in the machine and operating in timed relationship therewith for rendering said other means ineffective to move certain of said members into position to engage said sequentially fed devices while enabling said other means to remain effective to move others of said members into position to en-

gage said sequentially fed devices for movement along said guideway, said carrier comprising a plurality of sections and including means cooperating with one of said sections for moving one of said carrier sections and one of sequentially fed devices carried thereby from one of said stations through an intermediate station to another of said stations therebeyond while during the same movement of said carrier another section of said carrier is effective to move one of said sequentially fed devices carried thereby from one of said stations to the next adjacent one of said stations.

6. In a machine through which devices are sequentially fed to enable printing or control or like operations to be performed in the machine from or under control of said devices, a guideway, a station constituting a storage magazine for said devices arranged at a selected point along said guideway, a discharge station disposed on said guideway, an auxiliary printing station located at a selected point along said guideway between said magazine station and said discharge station, a main printing station arranged at a selected point along said guideway between said storage magazine station and said auxiliary printing station, a reciprocatory carrier movable along said guideway for sequentially advancing said devices from station to station along said guideway, means for reciprocating said carrier in advancing and returned directions along said guideway, means for effecting a printing operation from or under control of one of said devices arranged at said auxiliary station during a return movement of said reciprocatory carrier along said guideway in a direction away from said auxiliary printing station and toward said storage magazine station, and means for effecting a plurality of consecutive printing operations from or under control of another of said devices arranged at said main printing station during the same aforesaid return movement of said carrier.

7. In a machine through which devices are sequentially fed to enable printing or control or like operations to be performed in the machine from or under control of said devices, a guideway, a station constituting a storage magazine for said devices arranged at a selected point along said guideway, a discharge station disposed on said guideway, an auxiliary printing station located at a selected point along said guideway between said magazine station and said discharge station, a main printing station arranged at a selected point along said guideway between said storage magazine station and said auxiliary printing station, a reciprocatory carrier movable through advancing and returned movements along said guideway for sequentially advancing said devices from station to station along said guideway, means for reciprocating said carrier along said guideway, means for effecting a printing operation from or under control of one of said devices arranged at said auxiliary station during a return movement of said reciprocatory carrier along said guideway in a direction away from said auxiliary printing station and toward said storage magazine station, and means for effecting two consecutive printing operations from or under control of another of said devices arranged at said main printing station during the same aforesaid return movement of said carrier.

8. In a machine through which devices are sequentially fed to enable printing or control or like operations to be performed in the machine from or under control of said devices, a guideway,

a station constituting a storage magazine for said devices arranged at a selected point along said guideway, an auxiliary printing station located at a selected point along said guideway, a main printing station arranged at a selected point along said guideway between said storage magazine station and said auxiliary printing station, a reciprocatory carrier movable in opposite directions through an operative advancing movement and an idle return movement along said guideway for sequentially advancing said devices from station to station along said guideway, means for reciprocating said carrier along said guideway, means for effecting a printing operation from or under control of one of said devices arranged at said auxiliary station during a return movement of said reciprocatory carrier along said guideway in a direction away from said auxiliary printing station and toward said storage magazine station, means for effecting a plurality of printing operations from or under control of another of said devices arranged at said main printing station prior to the completion of the same aforesaid return movement of said carrier, an intermediate station arranged at a point along said guideway between said main printing station and said auxiliary printing station, a sensing station arranged at a point along said guideway between said storage magazine station and said main printing station, a plurality of pick-up devices movably mounted upon said carrier for advancing said printing or control or like devices from station to station along said guideway, said means for reciprocating said carrier being effective to cause said carrier to make a second reciprocation along said guideway after the reciprocation during which said plurality of consecutive printing operations are performed at said main printing station, and means for rendering said pick-up devices ineffective to advance printing or control or like devices from said storage magazine station to said sensing station and from said sensing station to said main printing station during the advancing movement of said carrier, in the second of said reciprocations of said carrier, in a direction away from said storage magazine station toward said auxiliary printing station, following the aforesaid return movement of said carrier in the first of said reciprocations of said carrier.

9. In a machine through which a plurality of devices bearing variable data are sequentially fed to enable operations to be performed in the machine from or under control of said devices, means for sensing variable data from said devices, a multiplying mechanism in the machine for performing a multiplying operation involving said variable data as a factor thereof, means under control of said multiplying mechanism for printing a product of said multiplying operation upon a sheet passed through said machine, means including a plurality of templet gangs for setting up said variable data in said multiplying mechanism as a factor of a multiplying operation to be performed therein, an additional or pilot templet associated with and settable with each of said templet gangs in accordance with digital values of said variable factor set up in said templet gangs, means associated with each of said additional or pilot templets for sensing therefrom the digital value set up on the corresponding one of said templet gangs, and variable data printing means settable under control of said sensing means for said additional or pilot

templets for printing said variable factor upon said sheet passed through the machine.

10. In a machine through which a plurality of devices bearing variable data are sequentially fed to enable operations to be performed in the machine from or under control of said devices, means for sensing variable data from said devices, a multiplying mechanism in the machine for performing a multiplying operation involving said variable data as a factor thereof, means under control of said multiplying mechanism for printing a product of said multiplying operation upon a sheet passed through said machine, means including a plurality of templet gangs for setting up said variable data in said multiplying mechanism as a factor of a multiplying operation to be performed therein, an additional or pilot templet associated with and settable with each of said templet gangs in accordance with digital values of said variable factor set up in said templet gangs, a sensing finger associated with each of said additional or pilot templets for sensing therefrom the digital value set up on the corresponding one of said templet gangs, a variable data printer including a plurality of type segments, and means under control of said sensing fingers for setting up said type segments in said variable data printer to print said variable data upon said sheet passed through the machine.

11. A machine as defined in claim 10 in which the means under control of said sensing fingers for setting up said type segments in said variable printer includes a plurality of digit-representing pinions and in which each of said sensing fingers when in its at rest position is retracted in an amount equivalent to the distance through which each of said sensing fingers moves to sense one digit from the particular one of said additional or pilot templets associated therewith so that each of said sensing fingers moves, upon initiation of an operation thereof, a distance sufficient to move the particular one of said digit-representing pinions controlled thereby from a normal at rest zero position into a position representative of the digit 9.

12. In a printing machine through which printing devices, each bearing identifying means and printing means, are adapted to be passed sequentially, a guideway along which such printing devices may be advanced, means for advancing such printing devices along said guideway in a step-by-step manner such that each printing device comes to rest at a sensing station and then at a printing station, said advancing means including engaging elements adapted to be rendered ineffective to advance printing devices from at least certain of said stations during an operating cycle of said advancing means, sensing means located at said sensing station operable to sense the identifying means of such a printing device, impression means located at said printing station and operable through a printing stroke to print an impression from the printing means of a printing device located at printing station, means for advancing a sheet to said printing station, and means operable under the control of said sensing means in accordance with the identifying means sensed thereby to control the operation of said impression means and said engaging elements.

13. In a printing machine through which printing and control devices, each bearing identifying means, control means, and printing means, are adapted to be passed sequentially, a guideway along which such printing and control devices may be advanced, means for advancing such

printing and control devices along said guideway in a step-by-step manner such that each printing and control device comes to rest at a sensing station and then at a printing station, sensing means located at said sensing station and comprising a first sensing head having means thereon operable to sense the control means on a printing and control device located at sensing station and said sensing means also including a second sensing head having means thereof for sensing the identifying means of such a printing and control device, impression means located at said printing station and operable through a printing stroke to print an impression from the printing means of a printing and control device located at printing station, means for advancing a sheet to said printing station, a variable printer set up under the control of said sensing means in accordance with a control means sensed thereby and operable to print the set-up data on such a sheet, and means operable under the control of said sensing means in accordance with the identifying means sensed thereby to control the operation of said variable printer and said impression means.

14. In a printing machine through which printing and control devices, each bearing identifying means, control means, and printing means, are adapted to be passed sequentially, the combination of a guideway along which such printing and control devices may be advanced, means for advancing such printing and control devices along said guideway in a step-by-step manner such that each printing and control device comes to rest at a sensing station and then at a printing station, said advancing means including engaging elements adapted to be rendered effective or ineffective to advance printing and control devices from certain of said stations, sensing means located at said sensing station and comprising a first sensing head having means thereon operable to sense the control means on a printing and control device located at sensing station and said sensing means including a second sensing head having means thereon for sensing the identifying means of such a printing and control device, impression means located at said printing station and operable through a printing stroke to print an impression from the printing means of a printing and control device located at printing station, means for advancing a sheet to said printing station, a variable printer set up under the control of said sensing means in accordance with a control means sensed thereby and operable to print the set-up data on such a sheet, and means operable under the control of said sensing means in accordance with the identifying means sensed thereby to control the operation of said variable printer, said impression means, and said engaging elements of said printing and control device advancing means.

15. In a printing machine through which printing and control devices, each bearing control means and printing means, are adapted to be passed in sequence to sensing and printing positions, advancing means operable to feed printing and control devices through the machine, impression means at said printing position operable through a printing stroke to print an impression on a sheet from the printing means of a printing and control device at printing position, a main control for the machine adapted in each cycle of operation of the control to cause operation of said impression means and said printing device advancing means, a supplemental control for the

machine operable to institute operation of said printing device advancing means during cycles when said main control is inactive, sensing means for sensing the identifying means and the control means of a printing and control device at sensing station, means controlled by said sensing means for governing the operation of said main control and said supplemental control, means for operating said sensing means whenever said printing and control device advancing means is operated, a variable printer for making impressions on sheets, settable members for controlling the setting of said variable printer, Bowden cable means controlling the setting of said settable members and moved from inactive positions to active positions by said sensing means in accordance with the control means sensed thereby, electrically operated means operable when energized to restore said Bowden cables to their inactive positions, and an energizing circuit for said electrically operated means adapted to be closed in timed relation to the operation of said printing and control device advancing means.

16. In a printing machine through which printing devices are adapted to be fed to a printing position, a variable printer located adjacent to said printing position, a main platen operable through a printing stroke for printing cooperation with a printing device located at said printing position, a supplemental platen separately mounted adjacent to said main platen for movement along a parallel path and movable through a printing stroke for printing cooperation with said variable printer, means for feeding sheets in succession to said printing position, means for actuating said main platen through a printing stroke, means for yieldingly urging both of said platens toward retracted inactive positions, means for feeding printing devices in succession into and then out of said printing position, control means operating in timed relation to the operation of said printing device feeding means to cause operation of said main platen through a printing stroke while a particular printing device is located at said printing station, means operable after such a printing stroke of said main platen to interconnect said supplemental platen with said main platen for actuation therewith, and control means operable to cause said main platen actuating means to operate said main platen and the interconnected supplemental platen through a second printing stroke to produce a printed impression from said variable printer after said printing device feeding means has advanced said particular printing device out of printing position.

17. In a printing machine having a sensing station and a printing station, feeding means for advancing printing and control devices to said sensing station and said printing station, a variable printer located at said printing station, sensing means operable to sense the control means of a printing and control device located at said sensing station and to set up said variable printer in accordance therewith, a platen at said printing station having a printing face adapted for cooperation with said variable printer to print the variable data set up in said variable printer, web advancing means operable to advance a web in a series of line spacing movements past said printing station, means operable to actuate said platen through a printing stroke to print variable data derived from a particular printing and control device prior to the time when the particular printing and con-

trol device reaches printing station, means for clearing said variable printer and operating said sensing means through another sensing operation to sense the control means of a succeeding printing and control device to thereby set up said variable printer in accordance with the control means of said succeeding printing and control device, means for operating said web advancing means through a line spacing movement prior to the time when said first mentioned printing and control device reaches printing station, means for causing another operation of said platen through a printing stroke to print the set up variable data derived from said succeeding printing device in the succeeding line of said web, and an additional printing face on said platen operable in said last mentioned printing stroke to print an impression from the printing means of said first mentioned printing and control device in said particular line while the newly set up variable data derived from said succeeding printing and control device is printed in the succeeding line of the web.

18. In a printing machine having a printing station, feeding means for advancing printing devices to said sensing station and said printing station, a variable printer located at said printing station, control means operable to set up in said variable printer variable data related to such a printing device, a platen at said printing station having a printing face adapted for cooperation with said variable printer to print the variable data set up in said variable printer, a web advancing means operable to advance a web in a series of line spacing movements past said printing station, means operable to actuate said platen through a printing stroke to print variable data related to a particular printing in a particular line of said web device prior to the time when the particular printing device reaches printing station, means for clearing said variable printer after a printing operation, means operable after such clearing operation to set up in said variable printer variable data related to a succeeding printing device, means for operating said web advancing means through a line spacing movement prior to the time when said first mentioned printing device reaches printing station, means for causing another operation of said platen through a printing stroke to print the set up variable data related to said succeeding printing device in the succeeding line of said web, and an additional printing face on said platen operable in said last mentioned printing stroke to produce a printing impression from said first mentioned printing device in said particular line while the newly set up variable data is printed in the succeeding line of the web.

19. In a printing machine through which printing and control devices, each bearing printing means and control means, are adapted to be fed in succession and in a step-by-step manner to a sensing station and then to first and second printing stations, a variable printer at said second printing station, sensing means operable to sense the control means of a printing and control device at said sensing station and to set up said variable printer in accordance therewith, platen means at said first printing station operable when a sensed printing and control device has advanced to said first printing station to print an impression from the printing means thereof onto a first sheet, means at said second printing station for feeding a web past said station parallel to the line of movement of the printing and control devices,

said web feeding movement being accomplished by a succession of line spacing movements of said web, a second platen means including an impression face positioned for cooperation with said variable printer, means for operating said second platen prior to the time when said sensed printing and control device reaches said second printing station, to thereby print the set up variable data in a particular line on said web, means operable after such printing of the variable data on the web to impart a line spacing movement to said web advancing means, and an additional platen face on said second platen aligned with the position to which said particular line on the web has been advanced, and printing device feeding means operable to locate each printing device at said second printing station for cooperation with said additional printing face to thereby cause the printing impression made from a printing and control device to be laterally aligned with the variable data impression made under the control of the control means of such printing and control device.

20. In a printing machine through which printing and control devices, each bearing identifying means, control means, and printing means, are adapted to be passed sequentially, a guideway along which such printing and control devices may be advanced, means for advancing such printing and control devices along said guideway in a step-by-step manner such that each printing and control device comes to rest at a sensing station, then at a first printing station, and subsequently at a second printing station, sheet feeding means for feeding sheets to said printing stations in a step-by-step manner, sensing means located at said sensing station operable to sense the control means and the identifying means on a printing and control device located at said sensing station, first and second variable printers located, respectively, at said first and second printing stations, means operable under the control of said sensing means in accordance with the control means sensed thereby to set up said variable printers, first and second impression means located at said first and second printing stations, respectively, and operable independently through printing strokes, the impression means at each of said stations including printing face portions adapted in a printing stroke of the impression means to cooperate with the adjacent variable printer to print variable data on a sheet, means controlled in part by said sensing means in accordance with the identifying means sensed thereby and in part by the sheet feeding means at said first printing station to render said impression means at said first printing station effective to produce printing impressions from said first variable printer and from the printing means of a printing and control device at said first printing station, said second impression means including a retractible printing face having active and inactive relations and adapted when active in a printing stroke of said second impression means to print an impression from the printing means of a printing and control device located at said second printing station, means operating in timed relation during operation of the machine to initiate printing strokes of said first and second impression means, governing means for controlling said retractible printing face to render the same inactive during a printing stroke of said second impression means, and at least two operation effecting means, either of which is operable to cause said governing means to render said re-

tractible printing face inactive, one of said operation effecting means being governed by the sheet feeding means at said second printing station in predetermined cycles of operation thereof, and the other of said operation effecting means comprising a storage means set up by said first impression means in accordance with the operation of said first impression means and operating in subsequent machine cycles to control said governing means.

21. In a printing machine through which printing and control devices, each bearing control means and printing means, are adapted to be passed sequentially, a guideway along which such printing and control devices may be advanced, means for advancing such printing and control devices along said guideway in a step-by-step manner such that each printing and control device comes to rest at a sensing station, then at a first printing station, and subsequently at a second printing station, sensing means operable to sense the control means on a printing and control device located at sensing station, first and second platens located at said first and second printing stations, respectively, and operable independently through printing strokes to print impressions from the printing means of printing and control devices located at the associated printing station, means for advancing sheets to said first printing station, means for advancing a web past said second printing station by a succession of line spacing movements, a variable printer located at said second printing station, means operable under the control of said sensing means in accordance with the control means sensed thereby to set up said variable printer, said second platen having a pair of printing faces offset with respect to each other in an amount equal to a line spacing movement of said web advancing means, one of said printing faces being adapted for cooperation with said variable printer to print variable data therefrom onto said web, and the other of said printing faces having disabling means associated therewith for rendering the same ineffective in a printing stroke of said second platen, means for operating said first platen through a printing stroke after a sensed printing and control device has reached said first printing station to print an impression from the printing means thereof onto a sheet, means operable to operate said second platen through a printing stroke prior to the time when said sensed printing and control device reaches said second printing station to thereby print the data set-up variable printer upon said web in a particular line, means operable to initiate a line spacing operation of said web advancing means after such printing of the variable data on said web, and means operable to cause another printing stroke of said second platen when said sensed printing and control device reaches said second printing station to thereby print an impression from the printing means of said sensed printing and control device in lateral alignment with the printed variable data derived from said printing and control device.

22. In a printing machine having feeding means operable to advance printing and control devices, each bearing printing means and control means, in succession and in a step-by-step manner to sensing and printing stations, web feeding means operable to advance a web past said printing station in step-by-step line spacing movements, impression means at said printing station operable through a printing stroke, a variable

151

printer located at said printing station, sensing means operable to sense the control means of a printing and control device at sensing station and operatively connected to said variable printer to set up the variable printer in accordance with the sensed control means, a pair of printing faces on said impression means adapted for cooperation respectively with said variable printer to print variable data and with the printing means of a printing and control device located at printing position to print changeable data, said variable printer and the cooperating printing face being offset in a direction parallel to the direction of web advancing movement with respect to the printing means of the printing and control device at printing station and the printing face cooperating therewith, whereby changeable data from one printing device are printed in one line on the web simultaneously with the printing in another line of variable data derived from another printing and control device.

23. In a printing machine through which printing and control devices are adapted to be fed in succession and in a step-by-step manner to a first printing station, then to an idle station and then to a second printing station so that a particular printing device may be disposed in said first printing station and a leading printing device may be disposed in said second printing station, means for feeding sheets of paper in succession to said printing stations, platen means at said first printing station operable through a plurality of printing strokes to print a plurality of impressions onto a sheet from a particular printing device located at said first printing station, a second platen means at said second printing station for cooperation with a leading printing device disposed at said second printing station, printing device feeding means operable through two feeding strokes in a machine cycle and operable in the first of said strokes to advance said particular printing device to said idle station and in the second of said strokes to advance said particular printing device to said second printing station, means to operate said second platen to print an impression from a leading printing device located at said second printing station while said particular printing device is still located at said first printing station, so that said feeding means may discharge said leading printing device from said second printing station in the feeding stroke in which said particular printing device is fed to said idle station, and means in said feeding means to so discharge said leading printing device.

24. In a printing machine through which printing and control devices are adapted to be fed in succession and in a step-by-step manner to a first printing station, then to an idle station and then to a second printing station so that a particular printing device may be disposed in said first printing station and a leading printing device may be disposed in second printing station, platen means at said first printing station operable through a plurality of printing strokes to print a plurality of impressions onto a first sheet from a particular printing device located at said first printing station, means at said second printing station for feeding a web past said second printing station, said web feeding movement being accomplished by a succession of line spacing movements of said web, a second platen means at said second printing station for cooperation with a printing device at said second printing station, printing device feeding means operable

152

through two feeding strokes in a machine cycle and operable in the first of said strokes to advance said particular printing device to said idle station and in the second of said strokes to advance said printing device to said second printing station, means to operate said second platen to print an impression on said web from a leading printing device located at said second printing station while said particular printing device is still located at said first printing station, so that said feeding means may discharge said leading printing device from said second printing station in the feeding stroke in which said particular printing device is fed to said idle station, and means in said feeding means to so discharge said leading printing device.

25. In a printing machine through which printing and control devices are adapted to be fed in succession and in a step-by-step manner to a first printing station, then to an idle station, and then to a second printing station, means for feeding paper to said printing stations to have printing impressions made thereon, first and second platens at said first and second printing stations, respectively, printing device feeding means operable through a first feeding stroke just prior to the mid-point of each machine cycle and operable through a second feeding stroke just prior to the end of each machine cycle, means for operating said second platen through a single printing stroke to form a printing impression from a leading printing device at said second printing station prior to said first feeding stroke of said printing device feeding means, means for operating said first platen through a plurality of printing strokes prior to said first feeding stroke of said printing device feeding means to make a plurality of printing impressions from a following printing device located at said first printing station, and engaging means on said printing device feeding means operable in said first feeding stroke to discharge said leading printing device from said second printing station and to advance said following printing device to said idle station, said engaging means operable in the second feeding stroke of said printing device feeding means to advance still another printing device into said first printing position and to advance said following printing device into said second printing station.

26. In a printing machine through which printing and control devices, each bearing control means and printing means, are adapted to be fed sequentially to a sensing position and then to first and second printing positions, first and second variable printers disposed respectively at said first and second printing positions, impression means at said first and second printing positions adapted for printing cooperation with the associated variable printer and with printing devices located at the associated printing position, multi-order means settable to represent multiple order variable numerical amounts, sensing means for sensing the control means of a printing and control device located at sensing position, means operable under control of said sensing means for controlling the setting of said settable means, a set up member for each order of each variable printer, means for latching the set up members in corresponding orders of the two variable printers together for set up movement in unison, means for each order of the variable printers operatively connected to the set up member in that order of said first variable printer, said last mentioned means being operable in accordance with

153

the setting of the corresponding order of said settable means to thereby set up the latched pairs of set up members in accordance with the set positions in the corresponding order of said settable means, accumulating means associated with said second variable printer adapted to be operatively associated order by order with the set up members of said second variable printer for entry into said accumulator of numerical amounts represented by the set up positions of the set up members of second variable printer, means for conditioning said accumulator selectively for either accumulating or total taking operation, and means operable after set up of all of said set up members to unlatch said set up members of said second variable printer from those of said first variable printer to thereby condition said second variable printer and its set up members for cooperation with said accumulator in a total taking operation.

27. In a printing machine through which printing and control devices, each bearing control means and printing means, are adapted to be passed sequentially, a guideway along which such printing and control devices may be advanced, means for advancing such printing and control devices along said guideway in a step-by-step manner such that each printing and control device comes to rest at a sensing station, then at a first printing station, and subsequently at a second printing station, sensing means located at said sensing station operable to sense the control means on a printing and control device located at sensing station, first and second impression means located respectively at said first and second printing stations, respectively, and operable independently through printing strokes to print impressions from the printing means of printing and control devices located at the associated printing station, means for advancing sheets to said printing stations, first and second variable printers located, respectively, at said first and second printing stations, means operable under the control of said sensing means in accordance with a control means sensed thereby to set up said variable printers in unison, means operating in timed relation to the operation of the sheet advancing means at one of said printing stations to print impressions from one of said variable printers on the sheet at one printing station, and means in said one variable printer operable thereafter to clear said one variable printer, means in the other of said variable printers operable at a different time in the machine cycle to print an impression on the sheet at the other of said printing stations and to thereafter clear said other variable printer, and means controlling the impression means of said stations to operate each impression means at the time when the variable printer at its station is to be operated.

28. In a printing machine through which printing and control devices, each bearing control means and printing means, are adapted to be fed sequentially to sensing position and then to first and second printing positions, first and second variable printers each embodying settable type segments and disposed respectively at said first and second printing positions, impression means at said first and second printing positions adapted for printing cooperation with the associated variable printer and with printing devices located at the associated printing position, multiple order means settable to represent multiple order variable numerical amounts, sensing means for sensing the control means of a printing and

154

control device located at sensing position, means operable under control of said sensing means for controlling the setting of said settable means, a set-up member for each order of each variable printer, each operable to set up the corresponding type segment in its variable printer, latch means in each order for latching the set-up members in its order of the two variable printers together for set-up movement in unison, a common operating means for said latch means, means in each order operatively connected to the set-up member in that order of said first variable printer and operable in accordance with the setting of the corresponding order of said settable means to set up the latched pairs of set-up members both in accordance with the set positions represented in the corresponding order of said settable means, accumulating means associated with said second variable printer adapted to be operatively associated order by order with the set-up members of said second variable printer for entry into said accumulator of numerical amounts represented by the set-up positions of the set-up members of second variable printer, means for conditioning said accumulator selectively for either accumulating or total taking operation, and means operable upon said common latch operating means after set-up of all of

29. In a printing machine through which printing and control devices, each bearing control means and printing means, are adapted to be fed sequentially to sensing position and then to first and second printing positions, first and second variable printers each embodying settable type segments and disposed respectively at said first and second printing positions, impression means at said first and second printing positions adapted for printing cooperation with the associated variable printer and with printing devices located at the associated printing position, multiple order means settable to represent multiple order variable numerical amounts, sensing means for sensing the control means of a printing and control device located at sensing position, means operable under control of said sensing means for controlling the setting of said settable means, a set-up member for each order of each variable printer, each operable to set up the corresponding type segment in its variable printer, latch means in each order for latching the set-up members in its order of the two variable printers together for set-up movement in unison, a common operating means for said latch means, means in each order operatively connected to the set-up member in that order of said first variable printer and operable in accordance with the setting of the corresponding order of said settable means to set up the latched pairs of set-up members both in accordance with the set positions represented in the corresponding order of said settable means, accumulating means associated with said second variable printer adapted to be operatively associated order by order with the set-up members of said second variable printer for entry into said accumulator of numerical amounts represented by the set-up positions of the set-up members of second variable printer, means for conditioning said accumulator selectively for either accumulating or total taking operation, and means operable upon said common latch operating means after set-up of all of

said set-up members to unlatch said set-up members of said second variable printer from those of said first variable printer to thereby condition said second variable printer and its set-up members for cooperation with said accumulator in a total taking operation, and operable while said set-up members of said second variable printer are unlatched to latch the type segments of said first variable printer in their set-up positions.

30. In a machine for producing business instruments and the like, a variable printer including settable type segments, a computing mechanism for determining numerical amounts to be printed and including settable members, the setting of each of which is indicative in a predetermined numerical notation of the digital value to be printed in a particular order, means for locating said settable members in initial positions indicative of the highest significant digit in such a notation, a transmitting pinion in each order adapted in a full rotation to represent two notations, means associated with said pinions defining zero positions and their initial highest digit positions for said pinions, means including sensing elements in each order operable to sense the set-up position of the settable member in its particular order and operable to rotate said pinions in a selected direction from their initial highest digit positions to set up positions, and means connected to said type segments to set the same and operable to turn said pinions in said selected direction from their initial or set positions to zero positions to thereby set up said type segments.

31. In a printing machine through which printing and control devices, each bearing control means and printing means, are adapted to be fed sequentially to sensing position and then to first and second printing positions, first and second variable printers each including settable type segments and disposed respectively at said first and second printing positions, impression means at said first and second printing positions adapted for printing cooperation with the associated variable printer and with printing devices located at the associated printing position, amount representing members settable to represent multiple order variable numerical amounts, printing device sensing means for sensing the control means of a printing and control device located at sensing position, means operable under control of said sensing means for controlling the setting of said amount representing members, a set up slide for each order of each variable printer, connecting latches for latching the set up slides in corresponding orders of the two variable printers together for set-up movement in unison, means in each order operable to sense the corresponding amount representing members and operatively connected to the corresponding set-up slide member in that order of said first variable printer to set up the slides and the associated type segments of the two variable printers in unison, first and second devices operable to latch the type segments of said first and second variable printers respectively in set up positions, means acting to render said first and second latch devices effective when said type segments have been set up, means operable to actuate said second impression means through a printing stroke while said first and second latch devices are both operative, a fourth latch operable to latch said first latch device in its active position, and means operable thereafter to release said connecting latches and render said second latch device inactive, said fourth latch

being operable to latch said connecting latches in released position.

32. In a printing machine having first and second printing positions, first and second variable printers each including settable type segments and disposed respectively at said first and second printing positions, impression means at said first and second printing positions adapted for printing cooperation with the associated variable printer amount representing members settable to represent multiple order variable numerical amounts, means for controlling the setting of said amount representing members, a set up slide for each order of each variable printer, connecting latches for latching the set up slides in corresponding orders of the two variable printers together for set-up movement in unison, means in each order operable to sense the corresponding amount representing members and operatively connected to the corresponding set-up slide member in that order of said first variable printer to set up the slides and the associated type segments of the two variable printers in unison, first and second devices operable to latch the type segments of said first and second variable printers respectively in set up positions, means acting to render said first and second latch devices effective when said type segments have been set up, means operable to actuate said second impression means through a printing stroke while said first and second latch devices are both operative, a fourth latch operable to latch said first latch device in its active position, means operable thereafter to release said connecting latches and render said fourth latch being operable to latch said connecting latches in released position, and means for releasing said fourth latch to release said first latch device and render said connecting latches operative.

33. In a printing machine through which printing and control devices, each bearing identifying means, control means, and printing means, are adapted to be passed in sequence to sensing and printing positions, feeding means for advancing printing and control devices through the machine, impression means at said printing position operable through a printing stroke to print an impression on a sheet from the printing means of a printing and control device at printing position, a single-cycle main control mechanism for the machine adapted in each cycle of operation of the main control mechanism to cause operation of said impression means and said printing device advancing means, a constantly operating supplemental control mechanism for the machine rendered ineffective for controlling operation by said main control mechanism during the cycle of operation of said main control mechanism and effective to institute operation of said printing device feeding means during cycles of said supplemental control mechanism when said main control mechanism is inactive, sensing means for sensing the identifying means and the control means of a printing and control device at sensing station, means for operating said sensing means whenever said printing and control device feeding means is operated, a selector relay adapted when energized to institute operation of said main control and adapted when restored to condition said supplemental control mechanism for controlling machine operation, an energizing circuit for said selector relay controlled by said sensing means in accordance with the identifying means sensed thereby, a selector restoring relay operable when

energized to condition said selector relay for subsequent operation, and an energizing circuit for said selector restoring relay adapted to be closed in timed relation to the operation of said printing and control device advancing means.

34. In a machine for producing business instruments and the like, a variable printer including settable type segments, a computing mechanism for determining numerical amounts to be printed and including settable members, the setting of each of which is indicative in a predetermined numerical notation of the digital value to be printed in a particular order, means for locating said settable members in initial positions indicative of the highest significant digit in such a notation, sensing means in each order operable to sense the set-up position of the settable member in its particular order, a shiftable setting element in each order and a shiftable positioning element in each order spaced therefrom and each having gear teeth thereon facing toward each other, a transmitting pinion disposed between said setting elements and positionable elements in each order and adapted for selective engagement with the gear teeth of said elements, said pinions being adapted in a full rotation to represent two notations, an operative connection between each setting element and the type segment of the corresponding order operable to impart set up movement to its type segment in accordance with the movement of the setting element, means acting when said sensing means is moved through a sensing stroke to operate said shiftable positioning element, means operable to shift said pinions into meshed engagement with the teeth of said positioning element during sensing operation of said sensing means to rotate said pinions in a selected direction to correspondingly set up said pinions and then with said setting elements, means for operating said setting elements to rotate said pinions in said selected direction to their zero positions, to thereby set up said type segments, means for returning the zeroized pinions to engagement with the teeth of said positioning member, and means operable thereafter to shift all of said pinions in said same selected direction to positions indicative of the highest significant digit of said notation.

35. In a machine for producing business instruments and the like, a variable printer including settable type segments, a computing mechanism for determining numerical amounts to be printed and including settable members, the setting of each of which is indicative in a predetermined numerical notation of the digital value to be printed in a particular order, means for locating said settable members in initial positions indicative of the highest significant digit in such a notation, sensing means in each order operable to sense the set-up position of the settable member in its particular order, a shiftable setting element in each order and a shiftable positioning element in each order spaced therefrom and each having gear teeth thereon facing toward each other, a transmitting pinion disposed between said setting elements and said positionable elements in each order and adapted for selective engagement with the gear teeth of said elements, an operative connection between each setting element and the type segment of the corresponding order operable to impart set up movement to its type segment in accordance with the movement of the setting element, means acting when said sensing means is moved through a sensing stroke to correspondingly operate said shiftable

positioning element, means operable to shift said pinions into meshed engagement with the teeth of said positioning element during sensing operation of said sensing means to set up said pinions and then to mesh the set up pinions with said setting elements, means for operating said setting elements to turn said pinions to their zero positions to thereby set up said type segments, means for returning the zeroized pinions to engagement with the teeth of said positioning member, and means operable to shift all of said pinions to positions indicative of the highest significant digit of said notation.

36. In a machine for producing business instruments and the like, a variable printer including settable type segments, reciprocable setting slides having operative connections with said type segments for setting up the same, transmitting pinions for each of said setting slides, said pinions in each full rotation being adapted to represent two full notations of a particular system of counting, a rack on each of said setting slides adapted to be engaged by one side of the corresponding transmitting pinion, a set-up segment disposed adjacent the other side of each of said transmitting pinions and adapted to be engaged thereby, shift-means for selectively engaging said transmitting pinions with said racks or said set-up segments, a stop element for said pinions, two stop members on each of said pinions for engagement with said stop element to define two zero positions for each of said pinions, a computing mechanism for determining numerical amounts to be printed and including settable members, the setting of each of which is indicative of the digital value to be printed in a particular order, means for locating said settable members in initial positions indicative of the highest digital value in said notation, sensing means in each order operable to sense the set-up position of the settable member in its particular order, means controlling said sensing means and also operable to shift said transmitting pinions into engagement with said set-up segments prior to sensing movement of said sensing means, means operable prior to operation of said sensing means to set said pinions in predetermined initial positions indicative of the highest digital value in said notation, an operative connection between each of said set-up segments and the sensing means in corresponding order, whereby in an operation of said sensing means said transmitting pinions are set in rotative positions indicative of the digital values represented by the set-up positions of said settable members, means operable thereafter upon said shifting means to engage said transmitting pinions with said set-up racks while maintaining said pinions in such set up position, and means operable thereafter to actuate said racks until each associated pinion reaches one of its zero positions, to thereby set up said type segments to print the numerical value represented by said settable members, and impression means for making an impression from the set-up type of said type segments.

37. In a machine for producing business instruments and the like, a variable printer including settable type segments, reciprocable set-up members for said type segments having geared connections with said type segments, set-up pinions for each of said set-up members, a rack on each of said set-up members adapted to be engaged by one side of the corresponding set-up pinion, a set-up segment disposed adjacent the other side of each of said set-up pinions and

adapted to be engaged thereby, shifting means for engaging said set-up pinions with said set-up racks or said set-up segments selectively, a stop element for said pinions, stop members on said pinions for engagement with said stop element to define zero positions for said pinions, a computing mechanism for determining numerical amounts to be printed and including settable members, the setting of each of which is indicative of the digital value to be printed in a particular order, means for locating said settable members in initial positions indicative of a predetermined digital value other than zero, sensing means in each order operable to sense the set-up position of the settable member in its particular order, means controlling said sensing means operable to shift said set-up pinions into engagement with said set-up segments prior to sensing movement of said sensing means, means operable prior to operation of said sensing means to set said pinions in predetermined initial positions indicative of the same digital value as said initial positions of said settable members, an operative connection between each of said set-up segments and the sensing means in the corresponding order, whereby in an operation of said sensing means said set-up pinions are set in rotative positions indicative of the digital values represented by the set-up positions of said settable members, means operable thereafter upon said shifting means to engage said pinions, while in such set-up positions, with said set-up racks, and means operable thereafter to actuate said racks until each associated pinion reaches its zero position, to thereby set up said type segments to print the numerical value represented by said settable members, and impression means for making an impression from the set-up type of said type segments.

38. In a machine for producing business instruments and the like, a variable printer including settable type segments, shiftable set-up members for said type segments operatively connected with said type segments, set-up pinions for each of said set-up members, gear teeth on each of said set-up members adapted to be engaged by one side of the corresponding set-up pinion, a set-up segment disposed adjacent the other side of each of said set-up pinions and adapted to be engaged thereby, shifting means for selectively engaging said set-up pinions with the teeth of said set-up members or said set-up segments, a stop element for said pinions, stop members on said pinions for engagement with said stop element to define zero positions for said pinions, a computing mechanism for determining numerical amounts to be printed and including settable members, the setting of each of which is indicative of the digital value to be printed in a particular order, means for locating said settable members in initial positions indicative of a predetermined digital value other than zero, sensing means in each order operable to sense the set-up position of the settable member in its particular order, means controlling said sensing means operable to shift said set-up pinions into engagement with said set-up segments prior to sensing movement of said sensing means, means operable prior to operation of said sensing means to set said pinions in predetermined initial positions indicative of the same digital value as said initial positions of said settable members, an operative connection between each of said set-up segments and the sensing means in corresponding order, whereby in an operation of said sensing

means said set-up pinions are set in rotative positions indicative of the digital values represented by the set-up positions of said settable members, means operable thereafter upon said shifting means to engage said pinions, while in such set-up positions, with the gear teeth of said set-up members, and means operable thereafter to actuate said set-up members until each associated pinion reaches its zero position, to thereby set up said type segments to print the numerical value represented by said settable members, and impression means for making an impression from the set-up type of said type segments.

39. In a printing machine through which printing and control devices, each bearing identifying means, control means and printing means, are adapted to be passed sequentially, a guideway along which such printing and control devices may be advanced, means for advancing such printing and control devices in a step-by-step manner along said guideway to bring each printing and control device to rest first at a sensing station, then at a printing station, an impression means located at said printing station adapted to make printing impressions from the printing means of printing and control devices located at said printing station, a first sensing means operable to sense the identifying means of printing and control devices located at the sensing station, variable printing means, additional sensing means operable to sense the control means of printing and control devices located at sensing station and to govern the set-up of said variable printing machines, means for operating both of said sensing means each time said printing and control device advancing means is operated, a main control for said machine operable to institute and control the operations of the operative mechanisms of the machine, said main control being normally inactive and being rendered active by said first sensing means to render said main control operative when printing impressions are to be made from a printing and control device sensed at sensing position, and a supplemental control for said machine arranged for constant operation and rendered effective under joint control of said first sensing means and said main control to govern the operation of said printing advancing means and said impression means in those cycles of operation wherein said main control is inactive.

40. In a printing machine through which printing and control devices, each bearing identifying means, control means, and printing means, are adapted to be passed sequentially, a guideway along which such printing and control devices may be advanced, means for advancing such printing and control devices in a step-by-step manner along said guideway to bring each printing and control device to rest first at a sensing station, then at a first printing station and subsequently at a second printing station, a first impression means located at said first printing station adapted to make printing impressions from the printing means of printing and control devices located at said first printing station, a second impression means at said second printing station operable to make printing impressions from the printing means of printing and control devices located at said second printing station, a first sensing means operable to sense the identifying means of printing and control devices located at the sensing station, variable printing means at one of said printing stations, additional sensing means operable to sense the control means of printing and control devices located at sensing

station and to govern the set-up of said variable printer, means for operating both of said sensing means each time said printing and control device advancing means is operated, a main control for said machine operable to institute and control the operations of the operative mechanisms of the machine, said main control being normally inactive, means under the control of said first sensing means to render said main control active when printing impressions are to be made from a printing and control device sensed at sensing position, and a supplemental control for said machine arranged for constant operation and rendered effective and ineffective under the joint control of said first sensing means and said main control to govern the operation of said printing advancing means and said second impression means in those cycles of operation wherein said main control is inactive.

41. In a printing machine having a printing device guideway along which printing and control devices may be advanced in a step-by-step manner to sensing position and to a succession of printing positions, impression means at said printing positions, feeding means for advancing printing and control devices along said guideway, sensing means at said sensing station, actuated means normally operable whenever said printing and control device feeding means operates to cause operation of one of said impression means, means effective under the control of the other impression means in one cycle of operation of the machine to disable said actuate means of said one of said impression means in a subsequent cycle of machine operation, a main control for the machine rendered active by and under the control of said sensing means when impressions are to be made from a particular printing and control device, said main control being rendered inactive by and under control of said sensing means when impressions from a particular printing device are not to be made, said main control being effective when active to institute operations of said printing and control device advancing means and said other impression means, and means rendered effective under control of said sensing means to institute operation of said printing and control device feeding means and said sensing means when said main control is inactive.

42. In a printing machine for producing business instruments and the like, and through which machine printing and control devices each bearing printing means, identifying means and control means may be passed seriatim to sensing position and then to first and second printing positions in the machine, means for feeding printing and control devices to said positions in a step-by-step manner, sensing means at said sensing station for sensing said identifying means and said control means of a printing and control device located at sensing station, means for feeding sheets of a first type to said first printing position and for feeding a second type of sheet to said second printing position, a first impression means at said first printing station operable through a printing stroke to print changeable data on a sheet of said first type located at said first printing position from the printing means of a printing and control device located thereat, a second impression means at said second printing station operable through a printing stroke to print changeable data upon a sheet of said second type located from a printing and control device located thereat, means governed by the identifying means sensed on a printing and con-

trol device while at sensing position to control the operation of said first impression means to govern the operation thereof when the printing and control device reaches said first printing position, and means governed by said first impression means to cause corresponding operation of said second impression means when the printing and control device reaches said second printing position.

- 10 43. In a printing machine for producing business instruments and the like, and through which machine printing and control devices each bearing printing means, identifying means and control means may be passed seriatim to sensing position and then to first and second printing positions in the machine, means for feeding printing and control devices to said positions in a step-by-step manner, sensing means at said sensing station for sensing said identifying means and said control means of a printing and control device located at sensing station, means for feeding sheets of a first type to said first printing position and for feeding a second type of sheet to said second printing position, a first impression means at said first printing station operable through a printing stroke to print changeable data on a sheet of said first type located at said first printing position from the printing means of a printing and control device located thereat, a second impression means at said second printing station operable through a printing stroke to print changeable data upon a sheet of said second type located from a printing and control device located thereat, means governed by the identifying means sensed on a printing and control device while at sensing position to control the operation of said first impression means to govern the operation thereof when the printing and control device reaches said first printing position, means governed by said first impression means to cause corresponding operation of said second impression means when the printing and control device reaches said second printing position, first and second variable printers located respectively at said first and second printing stations for cooperation with the impression means to print variable data upon the sheets fed to said stations, means under control of said sensing means to set up both of said variable printers from and under control of the control means carried by a printing and control device located at sensing station, and means controlling the feeding of said sheets to locate changeable data impressions and the variable data impressions on said sheets in predetermined relation.
44. In a machine for producing business instruments and the like, a variable printer including settable type segments, a computing mechanism for determining numerical amounts to be printed and including settable members shiftable from predetermined initial positions to set positions indicative of the digital value to be printed in a particular order, a transmitting pinion in each order adapted in a complete rotation thereof to represent at least one complete notation in a predetermined system of counting, means associated with said pinions defining zero positions for said pinions, a shiftable set-up element for rotating each pinion, means for operatively connecting said pinions with said type segments or said set-up elements selectively, sensing means including sensing elements for sensing the respective set positions of said settable members, transmitting means forming operative motion trans-
- 5 15 20 25 30 35 40 45 50 55 60 65 70 75

mitting connections between said sensing elements and the related set up elements, and actuating means for said transmitting connections operable when said pinions are connected to said set-up elements to move said sensing elements and rotate said pinions in a predetermined direction from their zero positions to initial positions representative of a predetermined value other than zero, said actuating means being thereafter operable upon said transmitting means to effect sensing cooperation of said sensing elements with said representing members to thereby rotate said pinions in said predetermined direction from said initial positions to set positions determined by the set positions of the related representing members, and operating means for actuating said type segments when said pinions are operatively connected to such segments to rotate said pinions in said predetermined direction from said set positions thereof to their zero positions to thereby set up said type segments.
